UNITED STATES PATENT OFFICE

2,297,092

TELEPHONE SYSTEM

John Wicks, Oak Park, Ill., assignor to Associated Electric Laboratories, Inc., Chicago, Ill., a corporation of Delaware

Original application September 26, 1938, Serial No. 231,780, now Patent No. 2,254,113, dated August 26, 1941. Divided and this application June 8, 1940, Serial No. 339,474

47 Claims. (Cl. 179—18)

The present invention relates to telephone systems and more particularly to improvements in repeating apparatus adapted for use in multi-exchange telephone systems comprising a plurality of interconnected small automatic exchanges and one or more central exchanges. The present application is a division of application Serial No. 231,780, filed September 26, 1938, now Patent 2,254,113, granted August 26, 1941.

It is an object of the invention to provide in a telephone system of the character described an improved alternating current impulse repeater chain adapted for use in controlling the automatic switching apparatus embodied in one exchange over a line terminating at another automatic exchange and wherein stepping switches are provided for controlling and responding to the control and supervisory pulses of alternating current transmitted between the repeaters in a positive and reliable manner.

It is a further object of the invention to provide an alternating current impulse repeater adapted for use in a telephone system of the character described and wherein the control of the seizing, release and supervisory operations is realized in an improved and exceedingly reliable manner.

It is a still further object of the invention to provide in a telephone system of the character described an improved and simple trunk circuit arrangement which may selectively be conditioned to operate in establishing connections on a manual to manual exchange basis between two operators' positions when the distant end of the associated trunk line is terminated at an operator's position or as a control circuit for an alternating current repeater when the distant end of the associated trunk line is terminated at an alternating current repeater.

The invention is illustrated as being embodied in a telephone system comprising a plurality of exchanges interconnected by trunk lines to form a loop network. Two of the exchanges have provided therein an operator's position and one of the trunk lines interconnecting the exchanges extends directly between the two operators' positions, whereby calls may be directly routed between the operators' positions over this one trunk line. At least a portion of the exchanges are of the automatic type, automatic switching apparatus being provided therein for the purpose of completing local connections between the subscribers' lines extending to the corresponding exchanges and for the further purpose of routing

toll calls to the respective operators' positions. Apparatus is also provided whereby the automatic switching apparatus located in two or more tandem connected exchanges is controllable from either of the two operators' positions to establish a connection to the other operator's position independently of the one trunk line mentioned above. Also, transfer switching apparatus is provided at the operators' positions for converting one of the two exchanges including an operator's position into a remotely controlled automatic tandem exchange on calls originating at or routed by way of the other operator's position and intended for a subscriber's line extending to another of the exchanges. This transfer switching apparatus is also arranged in an improved manner such that all calls intended for the operator's position in one of the two exchanges including an operator's position may be routed to the operator's position in the other exchange when the operator in the first-mentioned exchange is not on duty. The automatic switching apparatus respectively provided in the interconnected automatic exchanges is so connected and arranged that the same predetermined operation of the calling devices respectively provided at the automatic substations of the system causes connections to be forwarded to one or the other of the operators' positions. In other words, any automatic subscriber having a line included in the system may obtain the assistance of a toll operator by dialing a toll operator's directory number which is the same as regards all of the substations.

The trunk lines which interconnect the various automatic exchanges of the system are individually terminated at alternating current repeaters at each end thereof. Each of these repeaters comprises a stepping switch arranged in an improved manner to control the operation of the associated repeater in transmitting and responding to the various control and supervisory pulses of alternating current which are transmitted to and from the repeater when the associated trunk line is being used. More particularly and considering the two repeaters terminating the respective ends of an interoffice trunk line as first and second repeaters, respectively, when the first repeater is seized by the automatic switching apparatus provided in the same exchange, certain of the control relays embodied therein operate to cause a seizing pulse of alternating current to be transmitted over the associated trunk line to the second repeater. The control apparatus of the second repeater responds to the alternating

current seizing pulse by initiating the operation of the stepping switch embodied in the second repeater and by seizing the impulse responsive numerical switch associated with the second repeater. During impusing, the first repeater functions to convert the direct current impulses which are transmitted thereto into corresponding alternating current pulses which are reconverted into direct current impulses and transmitted to the seized numerical switch by the control apparatus of the second repeater. In accordance with one feature of the present invention, means are provided in the second repeater, operative in response to the operation of the stepping switch included therein to a predetermined off-normal position for releasing the second repeater in the event at least one pulse of alternating current, following the alternating current seizing pulse, is not transmitted to the second repeater before the stepping switch embodied in the second repeater is operated to a predetermined off-normal position. Means are also provided for arresting the operation of the stepping switch embodied in the second repeater and for causing this switch to be returned to its normal position in response to the first impulse of the first series of alternating current pulses transmitted to the second repeater over the associated trunk line. When the call as routed through the two repeaters in tandem is answered at a selected called subscriber the control apparatus embodied in the second repeater operates in response to the usual battery reversal over the trunk outgoing therefrom by operating to cause a supervisory pulse of alternating current to be transmitted over the trunk line interconnecting the first and second repeaters to the first repeater. The control relays of the last-mentioned repeater in turn operate to cause the exchange battery to be reversely connected to the conductors of the trunk line incoming to the first repeater. Also, the control apparatus embodied in the two repeaters is jointly operative, following the completion of the connection, to cause battery reversing operation to be performed, with respect to the trunk line incoming to the first repeater, each time the connection is broken or recompleted at the called telephone station. By virtue of this arrangement, control of the supervisory signal lamps located at a calling toll operator's position is effected.

In accordance with a further feature of the invention, the arrangement of the repeaters is such that two or more tandem-connected ones thereof are operative, in cooperation with the other automatic switches of an established switch train and under the control of an operator located at one of the toll operators' positions, to offer a toll call to the subscribers conversing over a busy called line. More particularly, the toll offering connection to the busy line is obtained in the usual manner by unbalancing one side of the trunk line incoming to the numerical switch having access to the called subscriber's line, the unbalancing of the trunk line being effected by impressing ground potential upon one of the trunk line conductors for a short time interval. To this end, the arrangement is such that, when the trunk line incoming to the first repeater of the two tandem-connected repeaters embodied in an automatic switch train is unbalanced, the control apparatus embodied in this first repeater operates to cause a supervisory pulse of alternating current to be transmitted over the associated trunk line to the distant second repeater

and also to initiate the operation of the stepping switch embodied in the first repeater. The duration of the pulse is under the control of the last-mentioned stepping switch, the pulse being terminated when this stepping switch is operated to a predetermined off-normal position. The length of the pulse is somewhat greater than the duration of the alternating current seizing pulse mentioned above and the control apparatus embodied in the second repeater responds to the supervisory pulse by operating at the end of the pulse momentarily to impress ground potential upon one of the line conductors of the trunk line incoming to the numerical switch having access to the busy called subscriber's line. The resulting operation of this numerical switch causes the desired connection to be established to the called line.

In accordance with a further feature of the invention, the stepping switches respectively embodied in the two tandem-connected repeaters of an automatic switch train are arranged jointly to control the release of the associated repeaters. More specifically, when a connection as routed by way of the first and second repeaters mentioned above is released at the calling end thereof the control apparatus embodied in the first repeater operates to cause a release pulse of alternating current to be transmitted over the associated trunk line to the distant second repeater and to again initiate the operation of the stepping switch embodied in the first repeater. The duration of this release pulse is substantially greater than the duration of the supervisory pulse mentioned above and is under the control of the stepping switch embodied in the first repeater, means being provided in this repeater operative in response to the operation of the indicated stepping switch to a predetermined off-normal position for terminating the alternating current release pulse and for initiating the release of the first repeater. The relay equipment embodied in the second repeater responds at the beginning of the alternating current release pulse by initiating the operation of the stepping switch embodied in the second repeater, means being provided in the second repeater operative in response to the operation of the last-mentioned stepping switch to a predetermined off-normal position for causing the release of the second repeater and for causing the indicated stepping switch to be returned to its normal position.

As indicated above, one of the trunk lines interconnecting the two exchanges having toll operators' positions therein extends directly between trunk circuit apparatus provided at the operators' positions respectively located in the two exchanges. In the main or central exchange this trunk line is permanently connected to one set of trunk circuit apparatus. In the other exchange the transfer means, mentioned above, is arranged selectively to connect the trunk line to the trunk circuit apparatus provided at the operator's position in this other exchange or to one of the alternating current repeaters briefly described in the preceding paragraph. Equipment is provided in the trunk circuit apparatus terminating the end of the trunk line extending to the central exchange for selectively conditioning this apparatus to be utilized in establishing connections to the operator's position in the other exchange when the trunk line is connected to the trunk circuit apparatus provided at the operator's position in the other exchange, and to

be utilized in routing connections through the alternating current repeater when the trunk line is connected to this repeater in the other exchange. More particularly, means are included in the trunk circuit apparatus terminating the trunk line in the central exchange for conditioning this apparatus to be utilized in establishing connections on a manual to manual exchange basis when the trunk line is connected to the trunk circuit apparatus provided at the operator's position in the distant exchange and for alternatively conditioning the first-mentioned trunk circuit apparatus to be utilized in established connections on an automatic to automatic exchange basis when the distant end of the trunk line is connected through the transfer means to the alternating current repeater provided in the distant exchange.

Further features of the invention pertain to the particular arrangement of the automatic switching apparatus whereby the above and additional operating features of the system are attained.

The novel features believed to be characteristic of the invention are set forth with particularity in the appended claims. The invention, both as to its organization and method of operation, together with further objects and advantages thereof, will best be understood by reference to the specification taken in connection with the accompanying drawings, in which Figures 1 and 2 schematically illustrate a system having the features of the present invention embodied therein; Fig. 3 illustrates the manner of assembling the remaining figures of the drawings to form a unified system in which the details of the system schematically shown in Figs. 1 and 2 are illustrated; and Figs. 4 to 35, inclusive, illustrate the details of the system schematically shown in Figs. 1 and 2.

SECTION 1.—GENERAL DESCRIPTION OF THE SYSTEM AND ITS OPERATION

Referring now more particularly to Figs. 1 and 2 of the drawings the system there shown comprises a plurality of exchanges A, B, C, D, E, and F of which the exchange A is a main or central exchange of the manual type and the remaining exchanges are subexchanges of the automatic type. For the purpose of handling toll calls routed to the exchange A, there is provided in this exchange an operator's position 10 having two sets of trunk circuit apparatus 10a and 10b located thereat. As indicated above, the arrangement of the system is such that certain of the toll calls are handled, under certain conditions, by an operator located in one of the smaller automatic exchanges. To this end there is provided in the exchange B an operator's position 14 which includes an operator's telephone station 15 and is arranged to be connected for service through the provision of transfer means in the form of a transfer switch 800 of the locking type. More particularly, this transfer switch is of the character such that when operated to one of its two operating positions, it remains in the operated position until manually actuated to its other operating position. The various enumerated exchanges are interconnected by trunk lines, in the manner illustrated, to provide a multi-exchange network. More particularly, the exchanges A and B are connected by a group of trunk lines including the trunk line indicated at 12; the exchanges B and F are connected by a group of trunk lines including the line indicated

at 42; the exchanges B and E are connected by a group of trunk lines including the line indicated at 31'; the exchanges B and C are connected by a group of trunk lines including the line indicated at 37; the exchanges C and D are connected by a single trunk line 65; and the exchanges A and D are connected by a group of trunk lines including the line indicated at 13. It will be observed that the trunk lines 12, 13, 10, 31 and 65 serve to interconnect the exchanges A, B, C and D to form a loop exchange network. In the exchange A the trunk line 12 terminates in the trunk circuit apparatus 10a. The other end of the trunk line 12 is arranged selectively to be connected, through operation of the transfer switch 800, to trunk circuit apparatus provided at the operator's position 14 or to a trunk line 28 extending to a two-way alternating current repeater 16.

20 Each of the enumerated exchanges has extending thereto a plurality of subscribers' lines having one or more substations individually associated therewith, and, with the exception of the exchange A, includes automatic switching apparatus for setting up connections between the various lines of the system and also between the subscribers' substations and the operators' positions 10 and 14. The subscribers' lines extending to the five automatic exchanges B, C, D, E and F include lines of the single and multiparty types. More particularly, these lines are of three different types, a part thereof being of the single party type having only one substation connected thereto, another portion thereof being of the well known duplex type having two substations individually associated therewith, and the remaining lines being of the well known multiplex type having more than two substations and automatic station selecting apparatus individually associated therewith. Only two of the lines which extend to the exchange B are illustrated in the drawings, these two lines being indicated at 33 and 34, respectively. As shown, the line 33 is of the single party type having a single substation T₃ associated therewith while the line 34 is of the duplex type having two substations T₁ and T₂ associated therewith. The lines 33 and 34 in the exchange B terminate in line circuits 21 and 22, respectively. The lines extending to the exchange C include two lines 59 and 60 terminating in line circuits 55 and 58, respectively. The line 59 is shown as being of the single party type having a substation T₄ associated therewith while the line 60 is of the duplex type and extends to two substations indicated at T₅ and T₆. The plurality of subscribers' lines extending to the exchange D includes two single party lines 74 and 75, respectively extending to the substations indicated at T₇ and T₈. These two lines respectively terminate in line circuits 71 and 68, respectively. Finally, the subscribers' lines extending to the exchange E include the two single party lines 76 and 77 having respectively associated therewith the substations T₉ and T₁₀. These two last mentioned lines are terminated in the exchange E in line circuits 78 and 79, respectively. The enumerated substations T₁ to T₁₀, inclusive, are all of the automatic type each including a calling or impulsing device of conventional design for transmitting switch control impulses over the associated line to the automatic switching apparatus provided in the exchange terminating the associated line.

For the purpose of establishing local connections between the subscribers' lines terminating at

the exchange B and for the additional purpose of routing connections to one of the two operators' positions 10 and 14 from calling ones of the sub-stations associated with lines terminating at the exchange B, there is provided in this exchange a plurality of local finder-connector links including the link indicated at 25. These links have commonly associated therewith a distributor 26 which is operative to assign idle ones of the links to calling ones of the lines terminating at the exchange B in a predetermined order. Each of the local finder-connector links includes a finder switch having access to each of the subscribers' lines terminating at the exchange B and also to each of the repeaters individually associated with the trunk lines extending between the exchanges B and C. Similarly, the connector portion of each of the local finder-connector links has access to each of the subscribers' lines extending to the exchange B and also to one or more trunk lines, such, for example, as the line 36, extending to trunk circuit apparatus provided at the operator's position 14. The connector switches of the local finder-connector links provided in the exchange B also have access to one or more repeaters individually associated with two-way trunk lines extending to the automatic switching apparatus provided in the exchange E. Thus, the connector portion of the link 25 is indicated as having access to a trunk line 38 terminating at a two-way repeater 20 which terminates one end of the interoffice trunk line 31' extending between the exchanges B and E. The connector switches respectively embodied in the local finder-connector links of the exchange B further have access to repeaters individually associated with trunk lines which are adapted to be connected by way of the transfer switch 800 to associated trunk lines extending to the exchange F. For example, the connector portion of the link 25 has access to a trunk line 31' extending to a repeater 18 terminating a trunk line 41 which is adapted to be connected through the springs of the transfer switch 800 to the trunk line 42 extending to the exchange F. By virtue of this arrangement and as explained in detail hereinafter, calls initiated on lines terminating at the exchange B and intended for lines terminating at the exchange F or the exchange E may be completed on an automatic to automatic sub-station basis without the intervention or assistance of either of the operators attending the operators' positions 10 and 14.

For the purpose of routing connections from the operator's position 10 in the exchange A through the exchange B to a subscriber's line terminating at one of the exchanges B, C, E and F or of routing connections from the operator's position 14 in the exchange B to one of the indicated subscribers' lines, there is provided in the exchange B a plurality of incoming connector switches, such, for example, as the switch 17, individually having incoming trunk lines terminating at the contact springs of the transfer switch 800. More particularly, the incoming connector switch 17 has incoming thereto a trunk line 30 which is adapted selectively to be connected through the contact springs of the transfer switch 800 to trunk circuit apparatus provided at the operator's position 14 or to a trunk line 29 extending to the alternating current repeater 16. The incoming connector switch 17 and the other switches of similar character have access to each of the subscribers' lines terminating at the exchange B. In addition, these switches have access to the trunk line 31' by way of which con-

nections may be routed through the repeater 20 to the automatic switching apparatus provided in the exchange E. The incoming connector switch 17 further has access to a trunk line 35 by way of which connections may be routed through the repeater 18 and over the trunk lines 41 and 42 to the automatic switching apparatus provided in the exchange F. Finally, the incoming connector switch 17 has access to a trunk line 32 extending to a two-way alternating current repeater 24 terminating one end of the trunk line 37 interconnecting the exchanges B and C. As explained in detail hereinafter, calls incoming to the exchange B from the two exchanges C and E are routed through the local finder-connector links provided in the exchange B. To this end the repeater 24 has extending thereto an outgoing trunk line 45 which terminates in a line circuit 23 and is connected to a link line 46 terminating in the bank contacts of the finder switches respectively embodied in the local finder-connector links provided in the exchange B. Similarly, the two-way repeater 20 associated with the trunk line 31' extending to the exchange E terminates a trunk line extending to a line circuit 21. The line circuit 21 also terminates a link line 47 extending to the bank contacts of the finder switches respectively embodied in the local finder-connector links provided in the exchange B. Normally, calls incoming to the exchange B from the exchange F are routed directly to the operator's position 14 located in the exchange B. When, however, the operator's position 14 is unattended such calls may be routed through the repeater 18 to a trunk selecting circuit 19, and from this trunk selecting circuit through the alternating current repeater 16, or another repeater identical therewith, to the operator's position 10 in the exchange A. More particularly and if the trunk lines 42 and 41 are utilized in forwarding the call to the operator's position in the exchange A, the repeater 18 functions to extend the connection over a trunk line 43 to the trunk circuit apparatus 19. The indicated trunk circuit is provided for the purpose of automatically selecting an idle one of two alternating current repeaters individually associated with trunk lines extending to the operator's position 10 in the exchange A. To this end the trunk circuit 19 is arranged to have access to a trunk line 44 extending to the repeater 16 and also to a trunk line 44' which is indicated as extending to a second repeater identical with the repeater 16.

Referring now more particularly to the automatic switch apparatus provided in the exchange C, the trunk line 37 extending between this exchange and the exchange B terminates at a two-way alternating current repeater 50 having extending thereto the conductors of a trunk line 61 incoming to an incoming connector switch 53 individually associated with the repeater 50. The incoming connector switch 53 has access to all of the subscribers' lines terminating at the exchange C and also to a repeater 57 terminating one end of the trunk line 65 extending to the exchange D. In a similar manner each of the other trunk lines extending between the exchanges B and C terminates at a two-way repeater identical with the repeater 50 and having associated therewith an incoming connector switch terminating the subscribers' lines extending to the exchange C. Calls routed through the automatic switching apparatus provided in the exchange D and over the trunk line 65 to the two-way repeater 57 located in the exchange

C may further be extended to a subscriber's line terminating at the exchange C or to the automatic switching apparatus provided in the exchange B through the provision of an incoming connector switch 56 which is individually associated with the repeater 57. More particularly, the incoming connector switch 56 has access to each of the subscribers' lines terminating at the exchange C and also to a trunk line 62 by way of which connections are routed through the two-way repeater 50 and over the trunk line 37 to the automatic switching apparatus provided in the exchange B. For the purpose of setting up local connections between the subscribers' lines terminating at the exchange C there is also provided in this exchange a plurality of switching selector repeater links and a plurality of local connector switches. One of the switching selector repeaters is indicated at 51 as having access to a local connector switch 54 which terminates only the subscribers' lines extending to the exchange C. It will be understood that a plurality of additional switching selector repeaters and local connector switches are provided in the exchange C in order that a number of calls may be handled at the same time. The switching selector repeater links have commonly associated therewith a distributor 52 which is operative in the usual manner to assign idle ones of the links for use in a predetermined order. The selector switches respectively embodied in the switching selector repeater links not only have access to the local connector switches through which local connections are set up between the substation lines terminating at the exchange C, but in addition have access to each of the two-way repeaters individually associated with the trunk lines extending to the exchange B. Thus, the switching selector repeater 51 is illustrated as having access to a trunk line 63 extending to the two-way repeater 50.

The automatic switching apparatus provided in the exchange D comprises a two-way alternating current repeater 66 terminating the trunk line 65 and a similar two-way alternating current repeater 72 terminating the trunk line 13 extending to the trunk circuit apparatus 10, located at the operator's position 10 in the exchange A. Each of the other trunk lines extending between the exchanges A and D terminates in a two-way repeater identical with the repeater 72 in the last mentioned exchange. The various two-way repeaters provided in the exchange D have individually associated therewith incoming connector switches by way of which connections may be routed to the subscribers' lines terminating at the exchange D. More particularly, the repeater 66 has associated therewith an incoming connector switch 69 having access to each of the subscribers' lines extending to the exchange D and also to a trunk line by way of which connections may be routed through the repeater 72 and over the trunk line 13 to the operator's position 10 in the exchange A. This incoming connector switch also has access to trunk lines individually extending to the other two-way repeaters through which connections may be routed to and from the exchange A. Similarly, the two-way repeater 72 has individually associated therewith an incoming connector switch 67 having access to the subscribers' lines extending to the exchange D and also to a trunk line over which connections may be routed through the repeater 66 and by way of the trunk line 65 to the automatic switching ap-

paratus provided in the exchange C. For the purpose of setting up local connections between the subscribers' lines extending to the exchange D, the automatic switching apparatus provided in this exchange also includes a plurality of local finder-connector links one of which is indicated at 70. These links have commonly associated therewith a distributor 73 which is operative to assign idle ones of the links to calling ones of the subscribers' lines in a predetermined order. The connector switches respectively embodied in the local finder-connector links provided in the exchange D not only have access to the subscribers' lines extending to the exchange D but, in addition, have access to each of the repeaters individually associated with the trunk lines extending to the exchange A, whereby connections may be routed from the subscribers' lines terminating at the exchange D to an operator's position located in the exchange A.

The automatic switching apparatus provided in the exchange E is substantially similar to that embodied in the exchange C and described previously. More particularly, this apparatus comprises a plurality of incoming connector switches individually associated with the trunk lines extending between the exchanges B and E and each having access to the subscribers' lines terminating at the exchange E. Thus, the interoffice trunk line 31' extends to an incoming connector switch 84 having access to all of the subscribers' lines terminating in the exchange E. The automatic switching apparatus provided in the exchange E further comprises a plurality of switching selector repeater links and a plurality of local connector switches which are utilized in establishing local connections between the subscribers' lines extending to this exchange. Thus, there is provided a switching selector repeater 80 which includes a finder switch at which all of the lines extending to the exchange E terminate and a selector switch having access to the local connector switches corresponding to and including the local connector switch 82. The selector portion of the switching selector repeater 80 also has access to trunk lines individually extending to the repeaters respectively associated with the interoffice trunk lines extending to the exchange B. For example, the switching selector repeater 80 has access to a trunk line 83 by way of which connections are routed through the incoming connector switch 84 and over the trunk line 31' to the automatic switching apparatus provided in the exchange B. In order to assign idle ones of the switching selector repeaters to the use of calling ones of the subscribers' lines extending to the exchange E, there is provided a distributor 81 which is operative to assign the available switching selector repeater links for use in a predetermined order.

The automatic switching apparatus provided in the exchange F for establishing local connections between the subscribers' lines extending to this exchange may, if desired, be substantially similar to that embodied in the exchange D and described above. In this case, however, the connector switches provided in the exchange F and having access to the trunk lines extending to the exchange B are arranged in a well known manner to project ringing current over a selected one of the trunk lines, such, for example, as the line 42, for the purpose of initiating the operation of the trunk circuit apparatus 19 or the trunk circuit apparatus normally terminating the selected line 75 at the operator's position 14.

Neglecting for the present the detailed circuit arrangement of the automatic switching apparatus briefly referred to above, and considering the operation of the system generally, it will be apparent that two types of calls, namely local and toll calls, are necessarily involved in a complete consideration of the manner in which the switching apparatus of the system operates. Considering first the mode of completing a connection between two substations associated with lines terminating at the exchange B and assuming that a call intended for the substation T₁ is initiated at the substation T₃, the operation of the automatic switching equipment provided in the exchange B to set up the desired connection is started when the calling subscriber at the substation T₃ removes his receiver from its hook to complete a loop circuit extending to the line circuit 27. The line circuit 27 responds to the completion of the calling loop circuit by operating to impress ground potential upon the start conductor of the distributor 26. The distributor 26 now operates to cause the finder portion of the assigned local finder-connector link to seize the calling line and to switch the calling loop circuit through to the control apparatus embodied in the link. Following the operation of the finder switch embodied in the assigned link to seize the calling line, the control apparatus of the link is conditioned to respond to the impulses of the first digit dialed at the calling substation and dial tone is returned to the calling subscriber. When the first digit is dialed at the calling substation the connector portion of the operated link functions to select the particular group of lines including the called line 34. Thereafter, and when the second digit is dialed at the calling substation, the connector portion of the operated link functions to select the particular called line from the selected group of lines. If this called line is busy at the time the connector switch of the operated link selects the same, the control apparatus of the operated link functions to return busy tone to the calling subscriber in the usual manner. On the other hand, if the called line is idle at the time it is selected, ringing current is projected thereover to energize the signal device provided at the called substation and the usual ring-back tone signal is returned over the calling loop circuit to the calling subscriber. Finally, the desired talking circuit between the calling and called substations is fully completed when the call is answered at the called substation, the control apparatus embodied in the operated link being responsive to this operation to arrest the ringing operation and to complete the desired talking connection. The arrangement of the local finder-connector links is such that the release of a local connection established in the manner just described is entirely under the control of the calling party. More particularly, when the calling subscriber at the substation T₃ hangs up, the loop circuit extending to the operated local finder-connector link is interrupted so that the relay apparatus provided therein operates to release the link and to initiate the release of the line circuit 27, whereby the calling line is marked as idle and is rendered accessible to the connector switches. The distributor 26 associated with the local finder-connector links provided in the exchange B is arranged to select an idle link for use immediately the finder portion of a previously assigned link operates to seize a calling one of the lines extending to the exchange B. Thus, when the call-

ing loop circuit extending the substation T₃ is switched through to the connector portion of a local finder-connector link assigned to the use of the line 33, the line circuit 27 operates to open the path over which ground potential is impressed upon the distributor start conductor and the control apparatus embodied in the assigned link operates to mark the link as busy in the distributor 26. At this time the distributor is caused to operate to select the next available idle one of the links for assignment to the use of the next calling line. Thus, the local finder-connector links are assigned to the use of successive calling lines in a predetermined order.

If the call as initiated at the substation T₃ in the manner explained in the preceding paragraph is intended for a substation associated with a line terminating at the exchange E, the desired connection may also be completed without the intervention of an operator. Thus, if the appropriate line selecting digits are dialed at the calling substation, the connector portion of the operated link, as, for example, the link 25, may be caused to operate to select an idle one of the repeaters, as, for example, the repeater 20, associated with a trunk line extending to the exchange E. On a trunk call of this character, the connector portion of the assigned link is arranged for switching through operation. More particularly, when the connector switch embodied in the link 25 seizes the trunk line 38, for example, extending to the repeater 20, the calling loop circuit is switched through to this repeater with the result that the repeater operates to establish a loop circuit extending by way of the trunk line 31' to the incoming connector switch 84. The incoming connector switch 84 responds to the completion of the last-mentioned loop circuit by conditioning itself to perform the desired line selecting operations in response to further digits dialed at the calling substation. The impulses of these additional digits are repeated by the control apparatus of the repeater 20 over the trunk line 31' to the control apparatus embodied in the incoming connector switch 84 and the last-mentioned apparatus responds thereto by selecting the desired subscriber's line. More particularly, the incoming connector switch 84 responds to the first series of impulses transmitted thereto by selecting the particular group of lines including the called line. Following the selection of this line group, the incoming connector switch 84 responds to the second series of impulses transmitted thereto by selecting the called line from the selected group of lines. Here again if the called line is busy at the time it is selected, the usual busy tone signal is transmitted back over the trunk line 31' through the repeater 20 and the local finder-connector link 25 and over the calling line 33 to indicate to the calling subscriber that the desired connection can not be obtained. On the other hand, if the called line is idle at the time it is selected, ringing current is projected thereover to energize the signal device provided at the called substation and the usual ring-back tone signal is returned to the calling subscriber to indicate that the called substation is being rung. Finally, the desired conversational circuit is completed and the ringing operation is arrested when the call is answered at the called substation. The release of a connection as routed from the substation T₃ through the incoming connector switch 84 to a substation line terminating at the exchange E is also under the control of the calling subscriber. Thus, when

the calling loop circuit is interrupted at the calling substation, the repeater 20 is released. During its release this repeater functions to remove holding ground potential from the control conductor of the trunk line 38 thereby to initiate the release of the local finder-connector link 25. Also, during its release the repeater 20 opens the loop circuit extending to the incoming connector switch 84 whereby this incoming connector switch is caused to restore to normal in the usual manner.

As indicated previously, the manner in which a connection may be routed from a calling subscriber's line terminating at the exchange B to a called subscriber's line terminating at the exchange F depends upon the position of the transfer switch 800. Thus, if the operator's position 14 in the exchange B is attended, a desired connection of the character indicated can only be completed with the assistance of the operator at this operator's position and in the manner explained subsequently. On the other hand, if the operator's position 14 is not attended and the transfer switch 800 occupies the position illustrated in the drawings, the connection may be forwarded to the desired called substation without the intervention of an operator. For example, if the call as initiated at the substation T₃ and routed by way of the local finder-connector link 25 is intended for a subscriber's line terminating at the exchange F and is initiated at a time when no operator is on duty at the operator's position 14, the calling subscriber may, by dialing the appropriate digits, cause the connector portion of the operated link 25 to seize the trunk line 37' extending to the two-way repeater 18. Here again, the local finder-connector link 25 operates to switch the calling loop circuit through to the indicated repeater immediately the trunk line 37' is selected and the control apparatus embodied in the repeater operates to place holding ground potential upon the control conductor of the trunk line 37', thereby to maintain the local finder-connector link operated. When the calling loop circuit is switched through to the repeater 18, this repeater also operates to complete a loop circuit extending by way of the trunk lines 41 and 42 to the automatic switching apparatus terminating the distant end of the trunk line 42 in the exchange F. When this last-mentioned loop circuit is completed, the seized switching apparatus provided in the exchange F is conditioned to respond to the impulses making up further digits dialed at the calling substation. From this point on, the manner in which the desired connection is completed and released is exactly the same as described above with reference to the call initiated at the substation T₃ and routed to a substation line terminating at the exchange E.

If the call as initiated at the substation T₃ and routed by way of the local finder-connector link 25, for example, is a toll call requiring the assistance of an operator, the calling subscriber may cause the connection to be forwarded to the operator's position 14 in the exchange B or to the operator's position 10 in the exchange A by dialing the digits of the directory number representing an operator's telephone station. The arrangement of the local finder-connector link 25 and of the other similar links is such that a trunk hunting operation on the part of the connector portion of the link is initiated for the purpose of selecting an idle trunk line extending to the operator's position 14 when the directory 75

number designating an operator's telephone station is dialed. More particularly, the arrangement of the links is such that any seized one thereof responds to the impulses of the directory number 01 to select an idle one of the trunk lines extending to the operator's position 14 providing all of these trunk lines are not busy. Thus, if the trunk line 36 is the first available idle trunk line of the group when the digits 0 and 1 are dialed at the calling substation T₃, the connector portion of the link 25 operates to seize the line 36 and to switch the calling loop circuit through thereto. The one of the two operator's positions 14 and 10 to which the connection is routed depends upon the position of the transfer switch 800. More particularly, if the operator's position 14 in the exchange B is attended, the call is forwarded to this operator's position. Thus, when the trunk line 36 is seized and the calling loop circuit is switched through, the trunk circuit apparatus terminating this trunk line at the operator's position 14 operates to impress holding ground upon the control conductor of the trunk line 36, thereby to hold the link 25 operated, and also to signal the operator that an incoming call on the trunk line 36 awaits attention. The operator may utilize the telephone substation equipment indicated at 15 to answer the call and to ascertain the particular connection or service desired by the calling subscriber. The manner in which the connection may be further extended from the operator's position 14 to a substation line terminating at one of the other exchanges in the system is explained hereinafter. In the case, just described, of a connection routed from the substation T₃ to the operator's position 14 in the exchange B, the release of the operated switch train is under the control of the calling subscriber. Thus, when the calling loop circuit is interrupted at the calling substation, the trunk circuit apparatus terminating the trunk line 36 at the operator's position 14 operates to give the operator a disconnect signal and to remove holding ground potential from the control conductor of the line 36. When ground potential is removed from this control conductor, the operated local finder-connector switch 25, as utilized in establishing the connection, is released.

As indicated above, when the operator normally handling calls at the operator's position 14 in the exchange B goes off duty or leaves her post, she operates the transfer switch 800 to the position illustrated in the drawings such that the trunk line 36 is connected through the springs of this switch to the trunk line 40 extending to the two-way repeater 16. Hence, if the toll call originating at the substation T₃ is initiated at a time when the operator's position 14 is not attended, the two-way repeater 16 is seized when the local finder-connector link 25 utilized in establishing the connection operates to switch the calling loop circuit through to the trunk line 36. When this repeater is seized, it operates to apply holding ground to the control conductor of the trunk line 36 and to transmit a relatively short seizing pulse of alternating current by way of the trunk lines 28 and 12 to the trunk circuit apparatus 10_a terminating the line 12 at the operator's position 10 in the exchange A. This trunk circuit apparatus responds to the alternating current seizing pulse by operating to energize a line signal lamp individual to the line 12, thus indicating to the operator on duty at the operator's position 10 that an incoming call on

the line 12 should be answered. The operator attending the operator's position 10 in the exchange A may now answer the call in the usual manner and converse with the calling subscriber over the established talking circuit to ascertain the particular service or substation desired by the calling subscriber. The manner in which the connection may further be extended from the operator's position 10 to a desired called substation associated with a line terminating at one of the other exchanges is explained hereinafter. The release of the connection as routed from the calling substation T₃ to the local finder-connector link 25 and the two-way repeater 16 to the operator's position 10 in the exchange A is partially under the control of the calling subscriber and partially under the control of the operator attending the operator's position 10. More particularly, when the calling loop circuit from the substation T₃ to the repeater 16 is interrupted, the repeater 16 is released and certain of the control relays embodied therein operate to cause a supervisory pulse of alternating current to be transmitted by way of the trunk lines 28 and 12 to the trunk circuit apparatus 10a. This trunk circuit apparatus responds to the supervisory pulse of alternating current by operating to energize a supervisory lamp embodied therein which is also individual to the line 12, thus indicating to the operator that the established connection is ready to be released. When the loop circuit extending through to the two-way repeater 16 is interrupted in response to the release of the connection at the calling substation T₃, the control relays embodied therein also operate to remove holding ground potential from the trunk line 40, thereby to initiate the release of the local finder-connector link 25 and the line circuit 27. The release of the trunk circuit apparatus 10a is effected only when the operator at the position 10 disconnects her cord circuit from the trunk circuit apparatus 10a. More particularly, when the operator clears out the connection the trunk circuit apparatus 10a is released and during its release operates to transmit a relatively long release pulse of alternating current back over the trunk line 12 to the repeater 16. The control apparatus of the repeater 16 responds to this alternating current pulse by operating to establish a loop circuit to the incoming connector switch 17, whereby this switch is seized, and by initiating the operation of the apparatus for forcibly releasing the repeater 16. Thereafter, the last-mentioned apparatus operates to release the repeater 16 and to open the loop circuit extending to the incoming connector switch 17, whereby the switch 17 is restored to normal.

The manner in which local connections are set up between the subscribers' lines terminating at the exchange D is substantially similar to the mode of establishing local connections between subscribers' lines terminating at the exchange B and described above. Thus, if it be assumed, for example, that the local finder-connector link 70 is utilized in establishing a connection between the lines 74 and 75 in response to a call initiated at the substation T₇, the operation of the distributor 73 to cause the finder portion of the link 70 to seize the calling line is initiated in response to the operation of the line circuit 71 resulting when the calling subscriber removes the receiver provided at the substation T₇ from its supporting hook or cradle. More particularly, when a calling loop circuit is established to the line cir-

cuit 71, ground potential is impressed upon the distributor start conductor, whereby the distributor 73 cooperates with the finder switch of the link 70 to cause this switch to seize the calling line 74. When the calling line is seized, the calling loop circuit is switched through to the connector portion of the link, dial tone is returned to the calling subscriber, the line circuit 71 operates to remove ground potential from the distributor start conductor and the control apparatus of the link operates to mark the link as busy in the distributor 73. The distributor now operates to select the next available idle one of the local finder-connector links for use in completing a second connection on the next incoming call. When the calling loop circuit is switched through to the connector portion of the link 70, the control apparatus embodied in the link is conditioned to respond to the operation of the calling device provided in the calling substation T₇. During the first series of impulses dialed at this substation, the connector portion of the link 70 operates to select the particular group of lines including the called line 75. When the second digit is dialed at the calling substation, the connector portion of the link 70 operates to select the called line 75 from the previously selected group of lines in which this called line is included. Following the selection of the called line, the control apparatus embodied therein operates to test the line for the purpose of determining the idle or busy condition thereof; to return the usual busy tone signal to the calling subscriber if the called line is busy; and to project ringing current out over the called line for the purpose of energizing the signal device provided at the called substation in the event the called line is idle. This control apparatus further operates to return the usual ring-back tone signal to the calling subscriber in the event the selected called line is idle and ringing current is projected thereover. The ringing operation is arrested and the desired conversational circuit is completed between the calling and called substations when the call is answered at the substation T₈. The release of the connection as established in the manner just described is under the control of the subscriber at the calling substation. More particularly, when the calling subscriber hangs up to open the calling loop circuit, the local finder-connector link is restored to normal, this link is marked as idle in the distributor switch 73, and the calling and called lines are marked as idle in the bank contacts of the connector switches having access thereto. During the release of the connection and when guarding ground potential is removed from the control conductor of the line 74, the line circuit 71 is restored to normal in the usual manner.

All toll calls initiated at substations associated with lines terminating at the exchange D are routed to the toll operator's position 10 provided in the exchange A, the trunk line 65 not being accessible to the local finder-connector links provided in the exchange and hence is not available for use in completing connections between the subscribers' lines terminating at the exchange and the operator's position in the exchange B. Thus, if the call originating at the substation T₇ and routed to the local finder-connector link 70, is intended for a toll operator's position, the calling subscriber dials the two digits of the directory number designating a toll operator's telephone station. Here again, the bank wiring arrangement of the connector switches respectively em-

bodied in the local finder-connector links provided in the exchange D is such that when a subscriber having a substation associated with a line terminating at the exchange D dials the directory number comprising the digits 0 and 1, the connection is forwarded over a trunk line to a toll operator's position in the exchange A. Also, the connector switches of the respective local finder-connector links are arranged for trunk hunting, thereby automatically to select an idle one of the trunks in the group extending to the exchange A in response to the dialing of the toll operator's directory number at the calling substation. Thus, when the calling subscriber at the substation T₇ dials the digits 0 and 1 in the order named, the connector portion of the local finder-connector link 70 automatically operates to select a repeater associated with an idle one of the trunk lines extending to the exchange A. Assuming, for example, that the repeater 72 is seized by the connector portion of the link 70, when this repeater is selected the calling loop circuit is switched through thereto and the control apparatus embodied in the repeater operates to impress holding ground upon the control conductor of the trunk line extending thereto from the link 70, thereby to hold the indicated link operated. The repeater 72 also functions to transmit a seizing pulse of alternating current over the trunk line 13 to the trunk circuit apparatus 10_b terminating the line 13 at the operator's position 10. This trunk circuit apparatus responds to the alternating current seizing pulse by energizing the line signal lamp included therein and individually associated with the trunk line 13, thus indicating to the operator at the position 10 that an incoming call on the trunk line 13 should be answered. When the call is answered by the operator attending the operator's position 10, the desired talking circuit is fully completed between the operator's telephone set and the calling substation T₇, whereby the operator may converse with the calling subscriber and ascertain the particular service or connection desired by the subscriber. The manner in which the connection may be further extended to a desired called substation associated with a line terminating at one of the other exchanges is described subsequently.

The release of the connection as routed from the substation T₇ to the operator's position 10 in the exchange A is partially under the control of the calling subscriber and partially under the control of the operator attending the operator's position 10. More particularly, when the calling subscriber hangs up to open the loop circuit extending through the local finder-connector link 70 to the repeater 72, the control apparatus embodied in this repeater operates to cause a relatively long pulse of alternating current to be transmitted over the trunk line 13 to the trunk circuit apparatus 10_b. This control apparatus also functions to remove ground potential from the control conductor of the trunk line incoming thereto from the connector portion of the local finder-connector link 70. Thus, the release of this link and of the line circuit 11 is initiated. The trunk circuit apparatus 10_b responds to the alternating current pulse transmitted thereto from the repeater 72 by operating to energize the supervisory lamp included in this apparatus and individual to the trunk line 13, thus indicating to the operator on duty at the position 10 that the connection routed by way of the trunk line 13 is ready to be released. When the opera-

tor disconnects her cord circuit from the trunk circuit apparatus 10_b, this apparatus is released and during its release operates to transmit a relatively long pulse of alternating current back over the trunk line 13 to the repeater 72. This last-mentioned pulse of alternating current is in the nature of a seizing pulse in so far as the repeater 72 is concerned, the control apparatus of the repeater responding thereto by operating to establish a loop circuit to the associated incoming connector switch 67, whereby this switch is seized. The apparatus embodied in the repeater 72 for forcibly releasing this repeater is also started into operation when the last-mentioned pulse of alternating current is transmitted to the repeater over the trunk line 13. After a predetermined time interval this apparatus functions to cause the release of the repeater and to open the loop circuit extending to the seized incoming connector switch 67, thereby to initiate the release of the connector switch. Thus, the connection is entirely released.

Referring now more particularly to the operation of the automatic switching apparatus provided in the exchange C to establish a local connection between two subscribers' lines terminating at this exchange, and assuming, for example, that a call intended for the substation T₆ originates at the substation T₄, the operation of the apparatus to establish the connection is initiated in the usual manner when the calling subscriber removes the receiver provided at the substation T₄ from its supporting hook or cradle. More particularly, when the last-mentioned operation is performed, a calling loop circuit is completed to the line circuit 55 whereby this line circuit operates to mark the calling line in the bank contacts of the finder switches respectively embodied in the switching selector repeaters and also to impress ground potential upon the start conductor extending to the distributor 52. This distributor now operates to cause the finder portion of the previously assigned switching selector repeater to search for the calling line. Thus, if the switching selector repeater link 51 is the link assigned to the use of the calling line, the operation of the finder switch embodied in this link is initiated when ground potential is impressed upon the start conductor extending to the distributor 52. This distributor now operates to cause the finder portion of the previously assigned switching selector repeater to search for the calling line. Thus, if the switching selector repeater link 51 is the link assigned to the use of the calling line, the operation of the finder switch embodied in this link is initiated when ground potential is impressed upon the start conductor extending to the distributor 52. Also, when this switching selector repeater is seized, the selector portion thereof operates automatically to select and seize a repeater associated with an idle one of the trunk lines extending between the exchanges B and C. For example, if the trunk line 37 is the first available idle trunk line in the group of trunk lines interconnecting the exchanges B and C, the selector portion of the switching selector repeater 51 operates to seize the trunk line 63 extending to the repeater 50. When the repeater 50 is seized in this manner, the control apparatus embodied therein operates to transmit a seizing pulse of alternating current over the trunk line 37 to the repeater 24 terminating the distant end of this trunk line in the exchange B. The repeater 24, in turn, responds to the seizing pulse of alternating current transmitted thereto by operating to complete a loop circuit extending by way of the link line 45 to the line circuit 23 individually associated with the trunk line 37. The line circuit 23 now operates to mark the link line 46 as a calling line in the bank contacts of the finder switches respectively embodied in the local finder-connector links provided in the exchange B. This line circuit also operates to

impress ground potential upon the start conductor extending to the distributor 26, whereby the operation of the finder switch embodied in a previously assigned one of the local finder-connector links is initiated. When the wipers of this finder switch encounter the contacts terminating the conductor of the link line 46, the operation of the finder switch is arrested and the loop circuit extending from the repeater 24 and by way of the link line 45, the line circuit 23 and the link line 46 is switched through to the connector portion of the link. Also, the line circuit 23 operates at this time to remove ground potential from the start conductor extending to the distributor 26 and the control apparatus of the seized local finder-connector link operates to mark the line as busy in the bank contacts of the distributor switch 26. Following the extension of the loop circuit from the repeater 24 to the operated local finder-connector link in the manner just described, no further operation of this equipment occurs until the dialing operation is started at the calling substation T₄. As indicated above, during the interval when the selector portion of the switching selector repeater 51 is operating to select an idle one of the trunk lines extending to the exchange B, the finder portion of the link operates to search for the calling line 59. When this calling line is found, the operation of the finder switch is arrested and the calling loop circuit is switched through to the control apparatus of the link. Following this switching through operation, the line circuit 55 operates to remove ground potential from the distributor start conductor, and the control apparatus of the switching selector repeater 51 operates to mark this switching unit as busy in the distributor 52. The distributor 52 now operates to select the next available idle switching selector repeater for use in completing a connection on the next call. The control apparatus of the switching selector repeater 51 responds to the impulses of the first digit dialed at the calling substation T₄ by operating to determine whether the call is of a local character or is a toll call intended for one of the toll operators' positions. This control apparatus also functions to repeat the impulses of the first digit over the trunk line 63 to the repeater 50 associated with the trunk line 37. The control apparatus embodied in this repeater operates to convert the received direct current impulses transmitted thereto over the trunk line 63 into corresponding pulses of alternating current which are transmitted by way of the trunk line 37 to the distant repeater 24. The control apparatus of the last-mentioned repeater, in turn, operates to reconvert the received pulses of alternating current into corresponding direct current impulses which are transmitted over the loop circuit comprising the link lines 45 and 46 to the connector portion of the operated local finder-connector link located in the exchange B. As a result, the connector switch of the operated local finder-connector link operates to select a particular group of lines in response to the impulses of the first digit dialed at the calling substation T₄. In the present case wherein the call is intended for the substation T₆ associated with the line 60, the operation of the operated local finder-connector switch provided in the exchange B is without effect since the response of the control apparatus embodied in the switching selector repeater 51 indicates that the call is of a local character. More particularly, at the end of the first series of impulses, the control apparatus

embodied in the switching selector repeater 51 operates to open the loop circuit extending by way of the trunk line 63 to the two-way repeater 50, thereby to initiate the release of this repeater, the trunk line 37, the repeater 24, the line circuit 23 and the operated local finder-connector link provided in the exchange B, all in the manner explained subsequently. The control apparatus embodied in the link 51 also functions, at the end of the first series of impulses, to cause the selector portion of the link automatically to select an idle one of the local connector switches provided in the exchange C. Assuming, for example, that the local connector switch 54 is the first available idle switch of this character, when this switch is selected by the selector portion of the link 51, a loop circuit is established thereto and the control apparatus thereof is conditioned to respond to the impulses of further digits dialed at the calling substation T₄. The impulses of these further digits are repeated by the control apparatus of the switching selector repeater 51 over the established loop circuit extending to the local connector switch 54. This connector switch responds to the impulses of the first series transmitted thereto by operating to select the particular group of lines including the called line 60. Finally, the local connector switch 54 responds to the impulses of the second series of impulses transmitted thereto and representing the third digit dialed at the calling substation by operating to select the called line 60 from the previously selected group of lines. When the called line is selected, it is tested by the control apparatus of the local connector switch 54 to determine the idle or busy condition thereof and if found busy, the usual busy tone signal is returned to the calling subscriber. On the other hand, if the line is idle, ringing current is projected thereover to energize the signal device provided at the called substation and the usual ring-back tone signal is returned to the calling subscriber. Finally, the desired talking circuit between the substations T₄ and T₆ is fully completed when the call is answered at the called substation, the control apparatus embodied in the local connector switch 54 being arranged to respond to this operation by operating to arrest the ringing operation and by performing the final line switching operation incident to the completion of the desired talking circuit. The release of the operated switch train extending between the calling substation T₄ and the called substation T₆ is entirely under the control of the calling subscriber. More particularly, when the connection is cleared out at the called substation T₆, the loop circuit extending to the switching selector repeater 51 is interrupted and this link restores to normal. During its release, the switching selector repeater 51 operates to open the loop circuit extending to the local connector switch 54 and to remove guarding ground potential from the control conductor of the calling line 59. Also, during its release the switching selector repeater is marked as idle in the distributor 52. When ground potential is removed from the control conductor of the line 59 the line circuit 55 is restored to normal and the calling line is marked as idle in the bank contacts of the connector switches having access thereto. When the loop circuit extending to the local connector switch 54 is interrupted, this connector switch is restored to normal in the usual manner. During its release the connector switch 54 operates to remove guarding ground potential from the control conductor of the called

line 60, whereby this line is also marked as idle in the bank contacts of the connector switches having access thereto and the line circuit 58 is restored to normal.

Toll calls initiated at substations associated with lines terminating at the exchange C are routed over the trunk lines extending between this exchange and the exchange B and through the automatic switching apparatus provided in the last-mentioned exchange to the toll operator's position 14 or to the toll operator's position 10 located in the exchange A. Thus, the switching selector repeater link 51 and the other links corresponding thereto only have access to the repeaters which are associated with the trunk lines extending to the exchange B and the local connector switches provided in the exchange C are only used in completing local calls. Hence, it will be apparent that the trunk line 65 extending between the exchanges C and D cannot be taken for use by the automatic switching apparatus provided in the exchange C on a call originating at a substation associated with a line terminating at this exchange. As pointed out above, the arrangement of the apparatus is such that each time a call is initiated on one of the lines terminating at the exchange C a connection is established over one of the inter-office trunk lines connecting this exchange with the exchange B to a local finder-connector link provided in the last-mentioned exchange. Thus and considering again the call as initiated at the substation T₄, if this call is a toll call requiring the assistance of one of the toll operators for completion, the calling subscriber dials the two digits of the above-mentioned directory number 01 designating a toll operator's telephone station. The impulses of the first digit are transmitted through the repeater chain comprising the two alternating current repeaters 50 and 24 to the seized local finder-connector link located in the exchange B. Assuming, for example, that the link 25 is assigned to the use of the call by the distributor 26, the connector portion of this link operates in response to the impulses of the first digit by selecting the group of trunk lines including the line 36 extending to the operator's position 14 located in the exchange B. In this case the number of impulses of the first digit is such that the control apparatus embodied in the switching selector repeater 51 does not operate, at the end of the digit, to open the loop circuit extending to the repeater 50. Also, the character of the digit is such that the control apparatus embodied in the switching selector repeater 51 does not operate to select an idle one of the local connector switches provided in the exchange C. When the second digit comprising a single impulse is dialed at the calling substation T₄, the two-way repeater 50 operates to transmit a corresponding pulse of alternating current over the trunk line 37 to the repeater 24. The last-mentioned repeater, in turn, operates to transmit a corresponding direct current impulse to the connector portion of the operated finder-connector link 25. The connector switch of the link 25, in turn, responds to the received impulse by operating to select an idle one of the trunk lines as, for example, the line 36 extending to the operator's position 14 located in the exchange B. From the preceding description it will be apparent that if the call under consideration is initiated at a time when the operator in the exchange B is on duty, the operation of the connector switch embodied in the link 25 to seize

the trunk line 36 and to switch the loop circuit through to this trunk line results in the energization of the line signal lamp individual to this trunk line and provided at the operator's position 14. Thus, the operator on duty at the position 14 is informed that an incoming call on the line 36 should be answered. Upon answering the call the desired conversational circuit between the operator's telephone station and the calling substation T₄ is fully established. Thus, the operator may converse with the calling subscriber to determine the particular service or connection desired. If the toll call originating at the substation T₄ is initiated at a time when the operator's position 14 is not attended, the connection is forwarded over the trunk lines 36 and 40 through the repeater 16 and over the trunk lines 28 and 12 to the operator's position 10 in the exchange A. Thus, in the last-mentioned case the transfer switch 800 is operated to a position such that the trunk line 36 is connected to the trunk line 40 and the trunk line 12 is connected to the trunk line 28. Hence, when the connector portion of the local finder-connector link 25 operates to switch the loop circuit extending from the repeater 24 through to the trunk line 36, the repeater 16 is seized and operates to transmit a seizing pulse of alternating current by way of the trunk lines 28 and 12 to the trunk circuit apparatus 10_a in the manner explained previously. The trunk circuit apparatus 10_a responds to the alternating current seizing pulse by energizing the line signal lamp individual to the line 12, thus indicating to the operator on duty at the position 10 that an incoming call on the trunk line 12 should be answered. The operator attending the position 10 may now answer the call and converse with the calling subscriber to determine the particular service or connection desired. If the toll call originating at the substation T₄ is routed to the operator's position 14 in the exchange B, the release of the operated switch train is primarily under the control of the calling subscriber. More particularly, when the connection is cleared out at the calling substation, the loop circuit extending to the switching selector repeater 51 is interrupted and this repeater is caused to restore. During its release, the switching selector repeater 51 removes guarding ground potential from the control conductor of the calling line 59, thereby to cause the release of the line circuit 55 and to mark the calling line 59 as idle. Also, during its release, the switching selector repeater 51 operates to mark itself as idle in the distributor 52 and to interrupt the loop circuit extending by way of the trunk line 63 to the operated repeater 51. When the last-mentioned loop circuit is interrupted, the control apparatus embodied in the repeater 50 operates to release this repeater and to transmit a relatively long pulse of alternating current over the trunk line 37 to the repeater 24 terminating the distant end of this trunk line. The repeater 24 responds to the relatively long pulse of alternating current transmitted thereto by restoring to normal. During the release of this repeater, the loop circuit which extends by way of the line 46, the line circuit 23, the line 45, the local finder-connector link 25 and the trunk line 36 to the trunk circuit apparatus terminating the last-mentioned trunk line at the operator's position, is interrupted. The trunk circuit apparatus terminating the trunk line 36 at the operator's position 14 now operates to energize the supervisory

lamp included therein and individual to the line 36, thus indicating to the operator on duty at the position 14 that the connection routed by way of this trunk line is ready to be released. Also, when the loop circuit extending by way of the trunk line 36 to the trunk circuit apparatus terminating this line is interrupted, this trunk circuit apparatus operates to remove holding ground potential from the control conductor of the trunk line 36, thereby to initiate the release of the local finder-connector link 25. During the release of the link 25 the line circuit 23 is restored to normal and the operated link is marked as idle in the distributor switch 25. Thus, the toll connection as routed to the operator's position 14 from the substation T₄ is completely released. On the other hand, if the toll call initiated at the substation T₄ is routed to the operator's position 10 in the exchange A, the release of the operated repeater 16 and of the trunk circuit apparatus 10_a provided at the operator's position 10 is under the control of the operator on duty at this position in the exchange A. More particularly, when the calling loop circuit extending from the substation T₄ to the switching selector repeater 51 is interrupted, this repeater, the line circuit 55, the repeater 50 and the repeater 24 are all released in the manner just explained. During the release of the repeater 24, the loop circuit extending through the operated local finder-connector link 25 to the two-way repeater 16 is interrupted. The control apparatus in the last-mentioned repeater now operates to remove holding ground potential from the control conductor of the trunk line 40, whereby the operated local finder-connector link 25 and the line circuit 23 are caused to restore. Also, when this loop circuit is interrupted, the control apparatus embodied in the two-way repeater 16 operates to cause a relatively long pulse of alternating current to be transmitted by way of the trunk lines 28 and 12 to the trunk circuit apparatus 10_a located at the operator's position 10. This trunk circuit apparatus now operates, in the manner previously explained, to energize the supervisory lamp provided at the operator's position 10 and individually associated with the trunk line 12, thus indicating to the operator attending this operator's position that the connection routed by way of the trunk line 12 is ready to be released. As previously described, the repeater 16 is effectively released when the loop circuit extending thereto from the repeater 24 and through the local finder-connector link 25 is interrupted. When, however, the operator on duty at the operator's position 10 clears out the connection at this position to initiate the release of the trunk circuit apparatus 10_a, this apparatus operates to transmit a relatively long pulse of alternating current over the trunk lines 12 and 28 to the repeater 16, thereby effectively to reseize this repeater. The repeater 16 responds to the last-mentioned alternating current pulse by operating to complete a loop circuit extending by way of the trunk lines 29 and 30 to the incoming connector switch 17, whereby this incoming connector switch is seized. This control apparatus embodied in the repeater 16 and provided for the purpose of forcibly releasing this repeater is also started into operation in response to the last-mentioned pulse of alternating current transmitted to the repeater 16 over the trunk lines 12 and 28. A predetermined time interval thereafter the apparatus for forcibly releasing

the repeater 16 operates to release this repeater and to open the loop circuit extending to the incoming connector switch 17, causing this incoming connector switch to be released. Thus, the toll connection as established between the substation T₄ and the operator's position 10 located in the exchange A is fully released.

The manner in which local connections are established between subscribers' lines terminating at the exchange E is substantially similar to the mode of completing local connections between the subscribers' lines extending to the exchange C as described above. Thus, considering a call originating at the substation T₉ associated with the line 76 and intended for the substation T₁₀, by way of example, the operation of the automatic switching apparatus provided in the exchange E to complete the desired connection is initiated when the calling subscriber at the substation T₉ removes the receiver provided at this substation from its associated supporting hook or cradle. More particularly, when the receiver at the substation T₉ is removed from its hook, a loop circuit is completed to the line circuit 78, causing this line circuit to operate to mark the calling line in the finder switches respectively embodied in the switching selector repeater links and to impress ground potential upon the start conductor extending to the distributor 81. Assuming that the switching selector repeater 80 is assigned by the distributor 81 to the use of the calling line, the operation of the finder switch embodied in this repeater is initiated when ground potential is impressed upon the distributor start conductor. When the wipers of this finder switch are operated into engagement with the contacts terminating the conductor of the line 76, the operation thereof is arrested and the calling loop circuit is switched through to the selector portion of the repeater. During the interval when the finder switch of the seized selector repeater is operating to search for the calling line, the selector portion of this repeater operates to select an idle one of the trunk lines extending from the exchange E to the exchange B. Assuming for example, that the trunk line 31' is the first available idle line extending to the exchange B, the operation of the selector portion of the switching selector repeater 80 is arrested when the wipers of the selector switch embodied in this repeater are operated into engagement with the contacts terminating the trunk line 83. This trunk line is, when idle, connected to the trunk line 31' through the contact springs of one of the switching relays embodied in the incoming connector switch 84. Also, the trunk line 31' is, when idle, connected by way of the contact springs of one of the relays embodied in the repeater 20 through to the line circuit 21. Hence, when the switching selector repeater 80 operates to select the link line 83 and to complete a loop circuit extending by way of this link line, the line circuit 21 is caused to operate to mark the link line 47 as a calling line in the bank contacts of the finder switches respectively embodied in the local finder-connector links provided in the exchange B. The line circuit 21, upon operating, also functions to impress ground potential upon the start conductor extending to the distributor 26, whereby the finder portion of a previously assigned finder-connector link, such, for example, as the link 25, is caused to operate to seize the marked calling line 47. Thus, when the switching selector repeater 80 operates to seize the trunk line 83,

a connection is automatically routed as far as one of the local finder-connector links provided in the exchange B and the seized link in this exchange is conditioned to respond to operation of the calling device provided at the calling substation. Here again, the character of the first digit dialed at the calling substation determines whether the connection will be routed to a local connector switch provided in the exchange E or to a toll operator's position in one of the exchanges A and B. During the impulses of this first digit, the control apparatus embodied in the switching selector repeater 80 operates to repeat the impulses over the established loop circuit comprising the trunk lines 83 and 31' to the operated local finder-connector link located in the exchange B. For example, if the link 25 is assigned to the use of the calling line 47, the impulses of the first digit are repeated to the connector portion of this link so that the connector switch of the link operates to select one of the groups of lines terminating thereat. In the present case wherein the connection is to be routed to the subscriber's line 71, the control apparatus embodied in the switching selector repeater 80 operates at the end of the first digit dialed at the calling substation automatically to select an idle one of the local connector switches provided in the exchange E and having access to the called line 71. This control apparatus further functions to interrupt the completed loop circuit extending by way of the trunk line 83 to the operated local finder-connector link located in the exchange B, thereby to initiate the release of this link in the manner explained subsequently. Assuming that the local connector switch 82 is the first available idle local connector switch, when the selector portion of the switching selector repeater 80 operates to seize the trunk line incoming to this switch, the control apparatus of the local connector switch 82 is conditioned to respond to the impulses of further digits dialed at the calling substation. During the dialing of the second digit at the calling substation T₉, the control apparatus of the switching selector repeater 80 operates to repeat the impulses to the local connector switch 82, which connector switch, in turn, responds to the repeated impulses by selecting the particular group of lines including the called line 71. Thereafter and when the third digit is dialed at the calling substation T₉, the local connector switch 82 operates to select the called line 71 from the selected group of lines. Following the selection of the called line, the control apparatus embodied in the local connector switch 82 operates to test the called line to determine the idle or busy condition thereof and to return busy tone to the calling subscriber in the event the line is busy. If the called line is idle at the time it is selected by the connector switch 82, ringing current is projected thereover to energize the signal device provided at the called substation and the usual ring-back tone signal is returned over the line 76 to the calling subscriber. Finally, the ringing operation is arrested and the desired talking circuit is completed when the call is answered at the called substation T₁₀. The release of the connection as established between the two substations T₉ and T₁₀ is entirely under the control of the calling subscriber. Thus, when the connection is cleared out at the calling substation T₉, the calling loop circuit extending to the switching selector repeater 80 is interrupted and this repeater restores to open the loop cir-

cuit extending to the local connector switch 82. During its release the switching selector repeater 80 also marks itself as idle in the distributor 81 and removes guarding ground potential from the control conductor of the calling line 76, whereby the line circuit 78 is restored to normal and the line is marked as idle. When the loop circuit extending from the switching selector repeater 80 to the local connector switch 82 is interrupted, the last-mentioned switch restores and removes ground potential from the control conductor of the called line 71, whereby the line circuit 79 is released and the line 71 is marked as idle. Thus, the connection is entirely released and the calling and called lines 76 and 71, respectively, are both marked as idle in the bank contacts of the connector switches having access thereto.

If the call as initiated at the substation T₉ is a toll call, the calling subscriber dials the two digits of the directory number designating an operator's telephone station. More particularly, the calling subscriber dials the directory number comprising the digits 0 and 1 so that ten impulses are delivered to the connector switch of the operated local finder-connector link 25 with the result that this connector switch operates to select the group of trunk lines including the line 36 extending to the operator's position 14 in the exchange B. When the first digit 0 is dialed, the control apparatus embodied in the switching selector repeater 80 does not operate to release the operated switch train including the finder-connector link 25 located in the exchange B. Moreover, when this particular digit is dialed, the switching selector repeater does not operate at the end thereof to select an idle one of the local connector switches provided in the exchange E. When thereafter the second digit comprising a single impulse is dialed at the calling substation, the switching selector repeater 80 operates to repeat the impulse over the trunk lines 83, 31' and 47 to the connector switch of the operated local finder-connector link 25. The connector switch of this link now operates to select an idle one of the trunk lines as, for example, the line 36 extending to the operator's position 14 located in the exchange B. From this point on the manner in which a connection is completed to the operator's position 14 in the exchange B or to the operator's position 10 in the exchange A is exactly the same as described previously with reference to the toll call initiated at the substation T₄. Here again, the release of the switch train extending as far as the operated local finder-connector link 25 is under the control of the calling subscriber located at the substation T₉. More particularly, when the connection is released at this substation, the loop circuit extending to the switching selector repeater 80 is interrupted causing this repeater to restore to open the loop circuit extending by way of the trunk lines 83, 31' and 47 and through the operated local finder-connector link 25 to the trunk circuit apparatus terminating the trunk line 36 or to the repeater 16 terminating the trunk line 40. In either case, when this loop circuit is interrupted, holding ground potential is removed from the control conductor of the trunk line 36, thereby to initiate the release of the local finder-connector link 25. During its release this local finder-connector link operates to remove guarding ground potential from the control conductor of the trunk line 41, whereby the line circuit 21 restores to normal to mark

the repeater 20 as idle in the bank contacts of the connector switches having access thereto. During the release of the switching selector repeater 80, ground potential is removed from the control conductor of the trunk line 83, whereby the trunk line 31' is marked as idle in the bank contacts of the switching selector repeaters having access to this trunk line. During its release, the switching selector repeater 80 also functions to mark itself as idle in the distributor switch 81 and to remove guarding ground potential from the control conductor of the line 78, thereby to initiate the release of the line circuit 78. Thus, the switch train extending from the substation T₉ through the local finder-connector link 25 is fully released.

As pointed out previously, when an operator is on duty at the operator's position 14 in the exchange B, the transfer switch 800 is operated to a position such that the trunk line 42 extending to the exchange F is terminated at trunk circuit apparatus located at the operator's position 14. Hence, toll calls originating on lines terminating at the exchange F are normally routed over one of the trunk lines in the group including the line 42 to the operator's position 14 in the exchange B, from which position the calls may be forwarded to any desired substation of the system under the supervision of the operator attending this operator's position. When, however, the operator's position 14 is unattended, the transfer switch 800 is operated to a position such that the trunk line 42 is connected to the trunk line 41 and, accordingly, toll calls routed over the trunk line 42 are extended by way of the repeater 18, the trunk circuit 19 and one of the two trunk lines 44 and 44' to the operator's position in the exchange A. More particularly, if the trunk line 42 is seized by the automatic switching equipment in the exchange F at a time when the operator's position 14 is unattended, ringing current is projected thereover, which current is conducted by way of the trunk line 41 through the repeater 18 and over the trunk line 43 to the trunk circuit 19. The apparatus of this trunk circuit responds to the ringing current transmitted thereto by operating to select an idle one of the trunk lines 44 and 44' providing both of these trunk lines are not in use. The trunk circuit apparatus 19 also functions to impress guarding ground potential upon the respective control conductors of the trunk lines 35 and 37', thereby to guard the repeater 18 against seizure by the connector switches provided in the exchange B. If both of the two lines 44 and 44' are busy, the apparatus embodied in the trunk circuit 19 operates to return busy tone to the calling subscriber to indicate that the desired connection can not be obtained. Assuming that the trunk line 44, for example, is idle, the trunk circuit apparatus 19 operates to establish a loop circuit by way thereof to the repeater 16 and also to complete a bridging path between the line conductors of the trunk line 43, thereby to arrest the ringing operation and to cause the talking loop to be extended to the repeater 16. The last-mentioned repeater responds to the completion of the loop circuit extending thereto and including the trunk line 44 by operating to transmit a seizing pulse of alternating current over the trunk lines 28 and 12 to the trunk circuit apparatus 10_a located at the operator's position 10 in the exchange A, whereby this trunk circuit apparatus is caused to operate to energize

5 the line signal lamp individually associated with the trunk line 12. When the operator answers the call, the desired conversational circuit is fully completed, so that the operator may converse with the calling subscriber to ascertain the particular service or connection desired by the calling subscriber. The connection may be further extended to a substation associated with a line terminating at one of the other exchanges of the 10 system in the manner explained hereinafter. The release of the connection as established between the calling subscriber's substation and the operator's position 10 is partially under the control of the calling party and partially under the control of the operator on duty at the operator's position 10. More particularly, when the calling subscriber hangs up, the automatic switching apparatus provided in the exchange F and by way of which the connection is routed is caused to 15 restore to normal. During the release of this apparatus, the loop circuit extending by way of the trunk lines 41 and 42 to the trunk circuit 19 is interrupted with the result that this trunk circuit restores to normal to open the loop circuit 20 extending by way of the trunk line 44 to the repeater 16. Also, during its release the trunk circuit 19 operates to remove guarding ground potential from the respective control conductors of the trunk lines 35 and 37', thereby to mark 25 these trunk lines as idle in the bank contacts of the connector switches having access thereto. When the loop circuit extending from the trunk circuit apparatus 19 to the repeater 16 is interrupted, this repeater restores to normal. During 30 its release the repeater 16 operates, in the manner previously explained, to transmit a relatively long pulse of alternating current to the trunk circuit apparatus 10_a located at the operator's position 10. Thus, the supervisory lamp provided at the operator's position 10 and individually associated with the trunk line 12 is energized to signal the operator that the connection 35 routed over the trunk line 12 is ready to be released. When, thereafter, the operator clears 40 out the connection, the trunk circuit apparatus 10_a operates to transmit another pulse of alternating current back over the trunk lines 12 and 28 to the repeater 16 with the result that this repeater and the incoming connector switch 17 are again seized. The operation of the apparatus 45 for forcibly releasing the repeater 16 is also initiated when the last-mentioned pulse of alternating current is transmitted to this repeater. Hence, after a predetermined time interval the 50 repeater 16 is released and the loop circuit extending to the incoming connector switch 17 is interrupted, causing the last-mentioned switch to be released. Thus, the automatic switching equipment utilized in establishing the connection 55 to the operator's position 10 is fully released and is rendered available for further use.

Referring now to the operation of the automatic switching apparatus embodied in the system to establish connections to the various subscribers' lines on calls routed thereto from the operator's position 14 in the exchange B and considering first the operation of the apparatus to establish a connection between the operator's telephone station 15 and a substation associated 60 with a line terminating at the exchange B, as, for example, the line 33, it is pointed out that when the operator's position 14 is attended, the transfer switch 800 occupies a position such that the incoming connector switch 17 may be directly seized by the operator on duty at this position.

Thus, to establish a connection to the subscriber's line 33, the operator on duty at the position 14 first operates the trunk-connect key individual to the trunk line 30, thereby to complete a loop circuit extending by way of this trunk line to the incoming connector switch 17. When this loop circuit is completed, dial tone is returned thereover to signal the operator that the dialing operation may be started. The seized connector switch 17 responds to the impulses of the first digit dialed at the operator's position by selecting the group of lines including the called line 33. Thereafter and when the second digit is dialed, the incoming connector switch 17 operates to select the called line 33 from the selected group of lines and to test this line to determine the idle or busy condition thereof. If the selected line is busy, the usual busy tone signal is returned to the operator to indicate that the called line is in use. On the other hand, if the called line is idle, ringing current is projected thereover in the usual manner to energize the signal device provided at the called substation, and the usual ring-back tone signal is returned to the operator to indicate that the called substation is being rung. Assuming that the call originated at another of the substations of the system and was only routed to the operator's position 14 to obtain the operator's assistance in completing the desired connection, the operator located at the operator's position 14 may, after the call is answered at the called substation T₃, establish a link or jumper connection between the calling and called talking circuits, thereby fully to complete the desired talking connection between the calling and called substations. Following the completion of this jumper connection, the supervisory lamps, associated with the trunk lines incoming to the operator's position 14 and included in the connection, are relied upon by the operator to indicate the condition of the connection. The arrangement of the trunk circuit apparatus normally terminating the trunk line 30 at the operator's position 14 and of the incoming connector switch 17 is such that a toll call may be offered to a subscriber conversing over a connection involving a busy line. To this end there is provided in the trunk circuit apparatus terminating the trunk line 30 a toll offering switch which is operative to impress ground potential upon one side of the trunk line 30, thereby to unbalance an established loop circuit extending to the incoming connector switch 17. When this loop circuit is unbalanced, in the manner just described, the control apparatus embodied therein operates to establish a talking connection to the called line 33 even though this line is busy. Thus, the operator may break in upon the previously established connection and offer the toll call to the party conversing at the called substation. If the party to whom the toll call is offered accepts the call, the operator instructs the two parties conversing over the previously established connection to hang up; the arrangement being such that the release of the previously established connection is effected without interference due to the bridging connection established to the called line through the incoming connector switch 17. When the previously established connection is fully released, the called line 33 is marked as idle in the bank contacts of the incoming connector switch 17 with the result that this incoming connector switch operates to project ringing current over the line 33 to again energize the signal device provided at the called 75

substation T₃. Thereafter and when the call is answered at this substation, the desired conversational circuit is fully established between the operator's telephone station 16 and the substation T₃. The arrangement of the apparatus is such that reverse battery control is utilized for controlling the condition of the supervisory lamp associated with the link lines provided at the operator's position 14 and utilized by the operator in completing the above-mentioned jumper connection between the calling and called talking circuits. Thus, if the called subscriber at the substation T₃ desires to recall the operator attending the position 14 following the completion of the connection just described, he may do so by operating the switch hook provided at the called substation to interrupt and recomplete the loop circuit extending to this substation one or more times. Each time this loop circuit is interrupted and recompleted, the battery reversing relay embodied in the incoming connector switch 17 restores and reoperates. The trunk circuit apparatus terminating the trunk line 30 at the operator's position 14 responds to the restoration of the battery reversing relay embodied in the incoming connector switch 17 by operating to complete the circuit for energizing the supervisory lamp individual to the link line included in the established connection. Conversely, each time the battery reversing relay of the connector switch 17 reoperates, the trunk circuit apparatus terminating the trunk line 30 at the operator's position 14 operates to open the circuit for energizing the supervisory lamp individual to the connection. Thus, if the called subscriber at the substation T₃ operates the switch hook provided at this substation momentarily to interrupt the loop circuit extending by way of the called line 33 a plurality of times, the supervisory lamp individual to the established connection is repeatedly energized and the flashing of this lamp indicates to the operator that she is being recalled. The release of the connection as routed from the operator's position 14 to the substation T₃ is entirely under the control of the operator attending this operator's position. Thus, when the connection is cleared out at the called substation, the loop circuit extending to this substation is interrupted and the battery reversing relay embodied in the incoming connector switch 17 restores to reverse battery over the trunk line 30 to the trunk circuit apparatus terminating this trunk line at the operator's position 14. The trunk circuit apparatus now operates to complete the circuit for energizing the supervisory lamp individual to the link line utilized in establishing the link connection between the calling and called talking circuits. The continuous illumination of this lamp indicates to the operator that the connection is ready to be released. When the connection is cleared out at the operator's position, the loop circuit extending by way of the trunk line 30 to the incoming connector switch 17 is interrupted with the result that this incoming connector switch is restored to normal. During its release the connector switch operates to remove guarding ground potential from the control conductor of the subscriber's line 33, whereby the line circuit 27 is restored to normal and the line 33 is marked as idle in the bank contacts of the connector switches having access thereto.

If the call as initiated at the operator's position 14 and routed to the incoming connector switch 17 is to be extended to a substation associated with a line terminating at the exchange

E, the operator first dials the two digits designating the trunk lines forming the trunk line group interconnecting the exchanges B and E. The incoming connector switch 17 responds to the impulses of the first digit by operating to select the desired group of trunk lines. Thereafter and when the second digit is dialed, this switch operates automatically to select an idle one of the lines in the selected group. Assuming, for example, that the trunk line 31' is the 10 first available idle line in the group, the incoming connector switch 17 operates to seize the trunk line 31 and to switch the calling loop circuit through to the two-way repeater 20. When this loop circuit is completed, the control apparatus embodied in the repeater 20 operates to complete a loop circuit extending by way of the trunk line 31' to the incoming connector switch 84 located in the exchange E. The operation of the repeater 20 also results in the operation of the line circuit 21 to impress guarding ground potential upon the control conductor of the trunk line 38, thereby to mark the trunk line 31' as busy in the bank contacts of the other connector switches having access to this line. When the loop circuit extending by way of the trunk line 31' to the incoming connector switch 84 is completed, this connector switch is conditioned to respond to further impulses dialed at the calling operator's telephone station. During the impulses of the third digit dialed by the operator, the repeater 20 operates to repeat the impulses to the incoming connector switch 84 with the result that the indicated incoming connector switch operates to select the particular group of lines including the called line. Similarly, during the impulses of the fourth digit dialed by the operator, the repeater 20 operates to repeat the impulses to the incoming connector switch 84 and this switch responds by selecting the desired called line from the previously selected group of lines. Assuming, for example, that the substation T₁₀ associated with the line 77 is the substation desired by the calling subscriber, the incoming connector switch 84 operates to select the line 77 and to test the same to determine the idle or busy condition thereof. If the called line is idle, ringing current is projected thereover to energize the signal device provided at the called substation and the usual ring-back tone signal is returned to the operator to indicate that the called substation is being rung. Finally, the talking circuit between the called substation T₁₀ and the operator's telephone station 15 is completed when the call is answered at the called substation. By utilizing one of the link lines provided at the operator's position 14, the operator may establish a link or jumper connection between the calling and called talking circuits, thereby to complete the desired talking connection between the calling and called substations. If the called line 77 is busy at the time it is selected by the incoming connector switch 84, the usual busy tone signal is returned to the operator's position 14 to indicate to the operator that the called line is already occupied with a call. Upon receiving busy tone, the operator may either release the established connection extending to the called line or break in upon the previously established connection and offer the toll call to the subscriber located at the called substation. Assuming that the operator elects to offer the toll call to the party at the called substation, she may do so by operating the toll offering switch 75

embodied in the trunk circuit apparatus terminating the trunk line 30, thereby to unbalance the loop circuit extending through the incoming connector switch and by way of the trunk line 31 to the repeater 20 in the manner previously explained. The control apparatus embodied in the repeater 20 responds to the unbalanced condition of the loop circuit incoming thereto by operating to impress ground potential upon one of the conductors of the trunk line 31', thereby to unbalance the loop circuit extending to the incoming connector switch 84. When this last-mentioned loop circuit is unbalanced, the control apparatus of the incoming connector switch 84 operates to establish a talking circuit to the called subscriber's line, whereby the operator at the operator's position 14 may converse with the party using the substation T₁₀ and offer the toll call to this subscriber. If the subscriber at the called substation accepts the toll call, the operator instructs the parties conversing over the previously established connection to hang up. When this previously established connection is cleared out, the automatic switching equipment by way of which the connection extends is released and the called line 77 is marked as idle in the bank contacts of the incoming connector switch 84. The incoming connector switch 84 now operates to project ringing current over the called line 77 for the purpose of energizing the signal device provided at the called substation. Finally, when the call is answered at this substation, the ringing operation is arrested and the desired talking circuit extending to the operator's telephone station 15 is fully completed. Following the completion of a connection between the substation T₁₀ and another calling substation of the system on a call routed by way of the operator's position 14, supervision of the connection is provided by the supervisory signal lamp individually associated with the link line utilized in establishing a jumper connection between the calling and called talking circuits. Here again, reverse battery control is utilized for the purpose of controlling the condition of the indicated supervisory lamp. Thus, if the called subscriber at the substation T₁₀ desires to recall the operator attending the position 14 after the talking connection extending to the substation T₁₀ from the calling substation is fully completed, he may do so by momentarily interrupting and recompleting the loop circuit extending to the called substation one or more times. Each time this loop circuit is interrupted, the battery reversing relay provided in the incoming connector switch 84 restores to reverse battery back over the trunk line 31' to the repeater 20. The battery reversing relay equipment embodied in the repeater 20, in turn, responds to the reversal of battery over the trunk line 31' by reversing battery back over the trunk lines 31 and 30 to the trunk circuit apparatus terminating the trunk line 30 at the operator's position 14. This trunk circuit apparatus responds to the last-mentioned battery reversal by operating to complete the circuit for energizing the supervisory lamp associated with the link line by way of which the established connection extends. Similarly, each time the loop circuit extending to the called substation is recompleted, the battery reversing relay embodied in the incoming connector switch 84 operates to again reverse battery over the trunk line 31' to the repeater 20 with the result that the battery reversing relay equipment em-

bodied in this repeater operates to again reverse battery over the trunk lines 31 and 30 to the trunk circuit apparatus terminating the trunk line 30 at the operator's position 14. This trunk circuit apparatus responds to the battery reversals of the last-mentioned character by operating to open the circuit for energizing the supervisory lamp individually associated with the link line in use. Thus, if the loop circuit extending to the called substation T₁₀ is momentarily interrupted a number of times, the supervisory lamp indicating the condition of the connection is intermittently energized to signal the operator that she is being recalled from the called substation. The release of the connection as routed from the operator's position 14 to the called substation T₁₀ is under the control of the operator attending the operator's position 14. More particularly, when the connection is cleared out at the called substation, the battery reversing relays of the incoming connector switch 84 and the repeater 20 cooperate to reverse battery over the trunk lines 31 and 30 to the trunk circuit apparatus terminating the last-mentioned trunk line, with the result that the supervisory lamp indicating the condition of the established connection is continuously energized to signal the operator that the connection is ready to be released. When the connection is cleared out at the operator's position 14, the loop circuit extending by way of the trunk line 38 through the incoming connector switch 17 and over the trunk line 31 to the repeater 20 is interrupted, whereby this repeater is caused to restore to open the loop circuit extending by way of the trunk line 31' to the incoming connector switch 84. During its release, the repeater 20 also functions to remove ground potential from the control conductor of the trunk line 31, thereby to initiate the release of the incoming connector switch 17. When the repeater 20 is returned to normal, the line circuit 21 is also released and guarding ground potential is removed from the control conductor of the trunk line 38, thereby to render the repeater 20 accessible to the connector switches provided in the exchange B. When the loop circuit extending to the incoming connector switch 84 is interrupted, this incoming connector switch restores to normal in the usual manner. During the release of the incoming connector switch 84, ground potential is removed from the control conductor of the called line 11, whereby this line is marked as idle in the bank contacts of the connector switches having access thereto and the line circuit 79 is released. Thus, the connection as established between the operator's position 14 and the called substation T₁₀ is fully released and the apparatus utilized in completing the connection is rendered available for further use.

It will be apparent from the preceding description that when the operator's position 14 is attended and the transfer switch occupies a position connecting the conductors of the trunk line 42 to trunk circuit apparatus provided at the operator's position 14, calls may be routed from the operator's telephone station 15 over the trunk line 42 and through the automatic switching equipment provided in the exchange F without utilizing any of the automatic switching apparatus provided in the exchange B. The manner in which such connections are established and released is substantially similar to the mode of establishing and releasing the above described

connection extending between the operator's telephone station 15 and the substation T₃.

If the call initiated at the operator's telephone station 15 is to be routed to a substation associated with a line terminating at the exchange C, such, for example, as the substation T₄ connected to the line 59, the operator, upon seizing the incoming connector switch 17, in the manner explained above, dials the two digits designating the group of trunk lines interconnecting the exchanges B and C. At the end of the second digit, the incoming connector switch 17 operates automatically to select and seize a repeater associated with an idle one of the selected group of trunk lines. For example, if the trunk line 37 is the first available idle line of the selected group, the incoming connector switch 17 operates to seize the trunk line 32 extending to the repeater 24 and to switch the calling loop circuit through to this repeater. When the repeater 24 is seized, the control apparatus embodied therein operates to impress holding ground potential upon the control conductor of the trunk line 32, thereby to maintain the incoming connector switch 17 operated, and also to transmit a seizing pulse of alternating current over the trunk line 37 to the repeater 50 terminating the distant end of this trunk line. The last-mentioned repeater responds to the seizing pulse of alternating current transmitted thereto over the line 37 by operating to complete a loop circuit extending by way of the trunk line 61 to the associated incoming connector switch 53. Thus, the switch train comprising the incoming connector switch 17, the two repeaters 24 and 50 and the incoming connector switch 53 is conditioned to respond to the impulses making up the line selecting digits designating the called line 59. During the operation of the calling device provided at the operator's telephone station 15 to transmit the impulses making up the two digits representing the directory number of the substation T₄, the control apparatus embodied in the repeater 24 responds to the received direct current impulses and operates to transmit corresponding pulses of alternating current over the trunk line 37 to the repeater 50. The relay equipment embodied in the repeater 50, in turn, reconverts the alternating current pulses into corresponding direct current impulses which are transmitted over the loop circuit comprising the trunk line 61 to the incoming connector switch 53. This incoming connector switch responds to the first series of impulses by operating to select the particular group of lines which includes the called line 59. During the impulses making up the second digit of the directory number designating the substation T₄, the incoming connector switch 53 operates to select the called line 59 from the previously selected group of lines. Following the selection of this line, the control apparatus embodied in the connector switch 53 functions to test the line for the purpose of determining the idle or busy condition thereof. Assuming the line to be idle, ringing current is projected thereto from the incoming connector switch 53 to energize the signal device provided at the called substation T₄ and the usual ring-back tone signal is returned through the operated switch train to the operator's position 14 to indicate to the operator that the called substation is being rung. Finally, the ringing operation is arrested and the desired talking circuit between the operator's telephone station 15 and the called substation T₄ is completed when the call is answered

at the last-mentioned substation. After the call is answered, the operator supervising the call at the operator's position 14 may complete a talking connection between the calling and called talking circuits, in the manner previously explained, by utilizing one of the link lines provided at the operator's position 14 for this purpose. After the connection between the calling and called substations is fully completed, the operator on duty at the position 14 may rely upon the supervisory signal lamp associated with the link line in use to indicate when the connection is ready to be released.

If the called line 59 is busy at the time it is selected by the incoming connector switch 53, the control apparatus embodied in this connector switch operates to return the usual busy tone signal over the partially established connection to the operator's telephone station 15, whereby the operator is informed that the called line is busy. The calling operator may now clear out the connection to initiate the release of the switch train set up in the manner just described, or she may break in upon the previously established connection including the called line 59 and offer the toll call to the party using the substation T₄. If the operator elects to offer the call to the party using the called substation T₄, she actuates the toll offering switch embodied in the trunk circuit apparatus terminating the trunk line 30, thereby to unbalance the loop circuit extending through the incoming connector switch 17 and over the trunk line 32 to the repeater 24. When this loop circuit is unbalanced, the control apparatus embodied in the repeater 24 operates to cause a supervisory pulse of alternating current to be transmitted over the trunk line 37 to the repeater 50. The length of this pulse is substantially greater than that of the alternating current seizing pulse mentioned above and is also greater than the duration of the individual alternating current switch control pulses transmitted to the repeater 50 during impulsion. The repeater 50 responds to the supervisory pulse of alternating current transmitted thereto by momentarily unbalancing the loop circuit extending by way of the trunk line 61 to the incoming connector switch 53. The last-mentioned switch, in turn, responds to the unbalanced condition of the loop circuit incoming thereto by operating to establish a bridging connection to the called line 59. When this bridging connection is established, the desired talking circuit extending between the operator's telephone station 15 and the called substation T₄ is completed, whereby the calling operator may break in upon the conversation being held over the previously established connection and offer the toll call to the party using the substation T₄. If the toll call is accepted, the operator instructs the two parties conversing over the previously established connection to hang up. During the release of the previously established connection including the called line 59, this line is marked as idle in the bank contacts of the incoming connector switch 53. The indicated incoming connector switch now operates to project ringing current over the called line 59, thereby to energize the signal device provided at the called substation. When the call is answered at this substation, the ringing operation is arrested and the desired talking circuit is fully established between this substation and the calling operator's telephone station 15.

As indicated above, after the operator on duty at the operator's position 14 completes the desired

5 talking circuit between the calling substation and the called substation T₄ and disconnects from the established talking circuit, she relies upon the supervisory lamp associated with the link line provided at the operator's position 14 and utilized in connecting the calling and called talking circuits together to inform her as to the condition of the connection. Thus, if the called subscriber at the substation T₄ desires to recall the operator attending the operator's position 14, he may do so by operating the switch hook provided at the substation T₄ momentarily to interrupt one or 10 more times the loop circuit extending to this substation. Each time this loop circuit is interrupted, the battery reversing relay provided in the incoming connector switch 53 operates to reverse battery over the trunk line 61 to the repeater 50, which repeater responds to the battery reversal by transmitting a relatively short supervisory pulse of alternating current over the trunk line 37 to the repeater 24. The repeater 24 responds to the relatively short alternating current supervisory pulse by reversing battery back over the loop circuit extending by way of the trunk line 32 and through the incoming connector switch 17 to the trunk circuit apparatus terminating the trunk line 30 at the operator's position 14. This trunk circuit apparatus responds to the last-mentioned battery reversal by operating to complete the circuit for energizing the supervisory lamp individually associated with the link line utilized in connecting the calling and called talking circuits together. In a similar manner, each time the loop circuit extending to the called substation T₄ from the incoming connector switch 53 is recompleted, the battery reversing relay embodied in the incoming connector switch 53 reoperates to again reverse battery over the trunk line 61 extending to the repeater 50. The repeater 50 responds by causing an additional relatively short supervisory pulse of alternating current to be transmitted over the trunk line 37 to the repeater 24. The last-mentioned repeater, in turn, responds to the additional alternating current supervisory pulse by again reversing battery over the loop circuit extending through the incoming connector switch 17 to the trunk circuit apparatus terminating the trunk line 30 to the operator's position 14. This trunk circuit apparatus, in turn, operates to open the circuit for energizing the supervisory lamp individually associated with the established connection. Thus, it will be apparent that if the loop circuit extending to the called substation T₄ is 15 momentarily interrupted a number of times, the supervisory lamp provided at the operator's position 14 and individual to the established connection is intermittently energized to transmit a flashing signal to the operator. This signal indicates to the operator that she is being recalled by the subscriber at the called substation T₄, whereupon she may reenter the connection and converse with the called subscriber to determine the particular service desired.

20 The release of the connection as established between the operator's position 14 and the called substation T₄ is entirely under the control of the operator attending the indicated operator's position. More particularly, if the called subscriber at the substation T₄ hangs up before the connection is cleared out at the operator's position 14, the loop circuit extending to this substation is interrupted, with the result that the battery reversing relay embodied in the incoming connector switch 53 operates to reverse

battery over the trunk line 61 to the repeater 50. This repeater responds, in the manner explained above, by causing a relatively short supervisory pulse of alternating current to be transmitted over the trunk line 37 to the repeater 24. The last-mentioned repeater, in turn, responds to the alternating current supervisory pulse by reversing battery over the loop circuit extending to the trunk circuit apparatus terminating the trunk line 30 at the operator's position 14. This trunk circuit apparatus, in turn, operates to complete the circuit for energizing the supervisory lamp individually associated with the established connection. The continuous illumination of this lamp indicates to the operator that the connection is ready to be released. When the connection is cleared out at the operator's position 14, the loop circuit extending through the incoming connector switch 17 to the repeater 24 is interrupted with the result that this repeater is released and the control apparatus embodied therein operates to remove holding ground potential from the control conductor of the trunk line 32, thereby to initiate the release of the incoming connector switch 17. During its release, the repeater 24 operates to transmit a relatively long release pulse of alternating current over the trunk line 37 to the repeater 50. The last-mentioned repeater responds to the received alternating current release pulse by restoring to normal and, during its restoration, operates to remove guarding ground potential from the respective control conductors of the trunk lines 62 and 63, and to open the loop circuit extending by way of the trunk line 61 to the incoming connector switch 53. When this last-mentioned loop circuit is interrupted, the incoming connector switch 53 is caused to release and, during its release, functions to remove ground potential from the control conductor of the called line 59, thereby to initiate the release of the line circuit 55 and to mark the called line 59 as idle in the bank contacts of the connector switches having access thereto. Thus, the connection as established between the operator's position 14 and the called substation T₄ is fully released and the switching apparatus utilized in setting up the connection is rendered available for further use.

Since the incoming connector switch 53 individually associated with the repeater 50 has access to the trunk line 64 extending to the two-way repeater 57 terminating one end of the inter-office trunk line 65, it will be apparent that the connection as routed to the incoming connector switch 53 in the manner just explained, may be further extended over the trunk line 65 and through the automatic switching equipment provided in the exchange D to a substation associated with a line terminating at the last-mentioned exchange. If such a connection is desired by the calling subscriber, the operator supervising the call at the operator's position 14, after dialing the two digits required for the selection of the trunk line 37 or a similar trunk line included in the trunk line group interconnecting the exchanges B and C, dials one additional digit comprising a single impulse, which digit designates the trunk line 65 interconnecting the exchanges C and D. The incoming connector switch 53 responds to the single impulse, which impulse is repeated thereto through the repeater chain in the manner explained previously, by operating to seize the trunk line 64 extending to the repeater 57. When this trunk

line is seized, the incoming connector switch 53 switches the loop circuit incoming thereto through to the repeater 57, thereby to complete a local loop circuit extending from the repeater 50 to the repeater 57. The repeater 57 responds to the completion of this local loop circuit by operating to transmit a seizing pulse of alternating current over the trunk line 65 to the repeater 66 terminating the distant end of the line 65 in the exchange D. The repeater 66 responds to the received alternating current seizing pulse by operating to complete a loop circuit to the incoming connector switch 69 individually associated therewith. When this loop circuit is completed, the incoming connector switch 69 is seized and conditioned to respond to impulses transmitted thereto by the repeater 66. After dialing the three digits designating the trunk line 65, the operator initiating the call at the operator's position 14 continues to dial the additional digits of the directory number designating the called subscriber's line terminating at the exchange D. For example, if the substation T₇ is desired by the calling subscriber, the final two digits dialed at the operator's telephone station 15 are the digits of the directory number designating the substation T₇. During the impulses of these two digits, the repeater 50 operates in the manner explained above to convert the received pulses of alternating current into corresponding direct current impulses which are transmitted over the local loop circuit extending through the incoming connector switch 53 to the repeater 57. This repeater, in turn, reconverts the direct current impulses into corresponding alternating current pulses which are transmitted over the trunk line 65 to the repeater 66. The last-mentioned repeater, in turn, reconverts the alternating current pulses into corresponding direct current impulses which are transmitted to the incoming connector switch 69. The connector switch 69 responds to the first series of impulses transmitted thereto by operating to select the group of lines including the called line 74. Thereafter and when the second series of impulses is transmitted to the incoming connector switch 69, this switch operates to select the called line 74 from the selected group of lines. When the line 74 is selected by the indicated incoming connector switch, the line is tested to determine the idle or busy condition thereof, and if idle, ringing current is projected thereover to energize the signal device provided at the called substation T₇. Also, the usual ring-back tone signal is transmitted back over the established connection to indicate to the calling operator that the called substation is being rung. When the call is answered at the called substation, the desired talking circuit is completed between this substation and the operator's telephone station 15, whereupon the operator may employ one of the link lines provided at the operator's position 14 to establish a bridging connection between the calling and called talking circuits. Thus, the desired talking connection between the calling and called substations is fully established. If the called line 74 is busy at the time it is selected by the incoming connector switch 69, busy tone current is returned through the operated switch train to signal the calling operator that the called line is in use. Upon receiving busy tone the operator may either clear out the connection to release the operated switch train or break in upon the previously established connection and offer the toll call

to the party conversing at the called substation. In order to offer the toll call to the party located at the substation T₇, the operator momentarily actuates the toll offering switch embodied in the trunk circuit apparatus terminating the line 30 to unbalance the loop circuit extending through the incoming connector switch 17 to the repeater 24, whereby the repeater 50 is caused to unbalance the loop circuit extending through the incoming connector switch 53 to the repeater 57, all in the manner explained previously. The repeater 57 responds to the unbalanced condition of the loop circuit extending thereto by operating to transmit a supervisory pulse of alternating current over the trunk line 65 to the repeater 66, which latter repeater, in turn, responds to the received alternating current supervisory pulse by unbalancing the loop circuit extending to the incoming connector switch 69. The incoming connector switch 69 now operates to establish a talking circuit to the called substation T₇, whereby the operator may break in upon the conversation ensuing over the previously established connection including the line 14 and offer the toll call to the party located using the called substation. Here again, if the toll call is accepted, the parties conversing over the previously established connection are instructed to hang up and, during the release of the previously established connection, the line 14 is freed and marked as idle in the bank contacts of the incoming connector switch 69. This incoming connector switch now operates to project ringing current over the line 74 for the purpose of energizing the signal device provided at the called substation. Also, the incoming connector switch 69 arrests the ringing operation and completes the desired talking circuit between the operator's telephone station 15 and the called substation T₇ when the call is answered at the called substation.

Following the completion of the desired talking connection between the calling and called substations, the supervisory lamp individual to the connection and located at the operator's position 14 is relied upon to inform the operator as to the condition of the connection. Thus, the called subscriber at the substation T₇ may recall the operator, in the manner previously described with reference to the call routed to the substation T₄, by operating the hook switch provided at the substation T₇ momentarily to interrupt the loop circuit extending to this substation one or more times. When this loop circuit is interrupted, the back bridge or battery reversing relay provided in the incoming connector switch 69 operates to reverse battery over the loop circuit extending to the repeater 66, causing this repeater to transmit a supervisory pulse of alternating current over the trunk line 65 to the repeater 57. The last-mentioned repeater, in turn, responds to the received alternating current supervisory pulse by reversing battery over the local loop circuit extending through the incoming connector switch 53 to the repeater 50. In a similar manner, each time the loop circuit extending to the called substation T₇ is recompleted, the battery reversing relay embodied in the connector switch 69 reoperates to reverse battery over the loop circuit extending to the repeater 66 with the result that this repeater transmits an additional pulse of alternating current over the trunk line 65 to the repeater 57. The repeater 57 responds to this additional pulse of alternating current by again

reversing battery over the loop circuit extending through the incoming connector switch 53 to the repeater 50. The manner in which the last-mentioned repeater, the repeater 24 and the trunk circuit apparatus terminating the trunk line 30 at the operator's position 14 sequentially operate to control the supervisory lamp individual to the connection in response to the successive battery reversals over the loop circuit extending between the repeaters 57 and 50 is exactly the same as set forth previously. Thus, it will be apparent that when the loop circuit extending to the substation T₇ is momentarily interrupted a number of times, the supervisory lamp individual to the established connection and provided at the operator's position 14 is intermittently energized to signal the operator attending this position that she is being recalled by the called subscriber. The release of the connection as established to the called substation T₇ is entirely under the control of the operator attending the operator's position 14. Thus, if the connection is released at the call substation T₇ before it is cleared out in the operator's position 14, the supervisory lamp individually associated with the connection is energized and remains energized to signal the operator that the connection is ready to be released. The manner in which the incoming connector switch 17, the repeater 24 and the repeater 50 are released when the connection is cleared out at the operator's position 14 is exactly the same as described above with reference to the call routed from the operator's position 15 to the substation T₄. During the release of the repeater 50, the loop circuit extending through the incoming connector switch 53 to the repeater 57 is interrupted, thereby to initiate the release of the last-mentioned repeater. During its release the repeater 57 operates to remove holding and guarding ground potential from the control conductor of the trunk line 64, whereby the release of the incoming connector switch 53 is initiated. Also, during its release, the repeater 57 functions to transmit a relatively long release pulse of alternating current over the trunk line 65 to the repeater 66. The repeater 66 responds to this alternating current release pulse by restoring to normal and, during its restoration, functions to interrupt the loop circuit extending to the incoming connector switch 69. When this last-mentioned loop circuit is interrupted, the incoming connector switch 69 restores to normal and, during its release, removes guarding ground potential from the control conductor of the called line 74, whereby this line is marked as idle in the bank contacts of the connector switches having access thereto and the line circuit 71 is restored to normal. Thus, the connection as established between the operator's position 14 and the substation T₇ is fully released.

As indicated previously, the automatic switching apparatus respectively provided in the exchanges B, C, D and E and the trunk line 65 interconnecting the two exchanges C and D may be utilized to establish a connection between the operator's position 14 in the exchange B and the operator's position 10 located in the exchange A. Normally, calls between these two operators' positions are routed over one of the trunk lines, as for example, the line 12 extending directly between two operators' positions. In cases of emergency, however, when the trunk lines extending directly between the exchanges A and B may for some reason be out of service, the

provision of the arrangement for routing connections between the indicated two operators' positions over an alternate route serves to preserve the communication facilities between the exchanges A and B. Thus, if the call as initiated in the operator's telephone station 15 and routed over the trunk line 65 through the repeater 66 to the incoming connector switch 69, in the manner explained in the immediately preceding paragraphs, is to be further extended to the operator's position in the exchange A, the calling operator located at the operator's position 14, after dialing the three digits designating the trunk line 65, continues to dial the two digits of the directory number designating a toll operator's position. More particularly, the final two digits dialed at the calling operator's position are the digits 0 and 1 and the incoming connector switch 69 responds to the impulses of these two digits by operating to select the group of trunk lines extending from the exchange D to the exchange A. At the end of the last digit, the incoming connector switch 69, which is arranged for automatic trunk hunting, also operates to select an idle one of the selected group of trunk lines. Assuming, for example, that the line 13 is the first available idle trunk line of the selected group, the connector switch 69, during its trunk hunting operation, seizes the repeater 72 associated with this trunk line. When the repeater 72 is seized, the incoming connector switch 69 switches the incoming loop circuit through to the repeater 72 to establish a local loop circuit extending between the two repeaters 66 and 72. The repeater 72 responds to the completion of this loop circuit by operating to transmit a seizing pulse of alternating current over the trunk line 13 to the trunk circuit apparatus 10b terminating the line 13 at the operator's position 10. The repeater 72 also operates at this time to mark itself as busy in the bank contacts of the various connector switches having access thereto. The trunk circuit apparatus 10b responds to the seizing pulse of alternating current transmitted thereto by operating to energize the line signal lamp individually associated with the trunk line 13, thereby to indicate to the operator attending the operator's position 10 that an incoming call on the line 13 should be answered. When the operator at the position 10 answers the call, the desired talking circuit between the operator's position 14 and the operator's position 10 is fully established.

The manner in which the operated switch train through which the talking circuit extending between the operator's position 10 and the operator's position 14 is released is substantially similar to the release of the connection described above with reference to the call routed to the substation T₇ from the operator's position 14. During the release of this switch train and when the repeater 66 restores to normal, the loop circuit extending through the incoming connector switch 69 to the repeater 72 is interrupted, with the result that the last-mentioned repeater restores to remove holding ground potential from the control conductor of the trunk line extending thereto from the incoming connector switch 69. Thus, the release of the indicated incoming connector switch is initiated. During its release, the repeater 72 also functions to transmit a relatively long release pulse of alternating current over the trunk line 13 to the trunk circuit apparatus 10b located at the operator's position 10. 75

The trunk circuit apparatus 10b now operates to energize the supervisory lamp individually associated with the trunk line 13, thereby to indicate to the operator attending the position 10 that the connection is ready to be released. When the operator at this position clears out the connection, the trunk circuit apparatus 10b is released, and during its release, operates to transmit a relatively long pulse of alternating current back over the trunk line to the repeater 72, with the result that the repeater 72 and the incoming connector switch 67 associated therewith are seized. The operation of the apparatus embodied in the repeater 72 for forcibly releasing this repeater is also initiated in response to the alternating current pulse transmitted to the repeater 72 over the trunk line 13. Hence, a predetermined time interval after the repeater 72 is seized, this repeater is released to initiate the release of the incoming connector switch 67. Following the release of the last-mentioned switch all of the apparatus utilized in setting up the connection between the operator's position 10 and the operator's position 14 is fully released.

From Fig. 1 of the drawings, it will be apparent that if the operator on duty at the operator's position 14 in the exchange B desires a connection with one of the operator's positions located in the exchange A she may seize one of the trunk lines in the group extending directly between the exchanges A and B. For example, the operator attending the operator's position 14 may seize the trunk line 12 extending to the operator's position 10 in forwarding a call to the exchange A. The trunk circuit apparatus terminating the respective ends of the trunk line 12 is such that the usual ring down operation is utilized in routing connections over this trunk line between the two operators' positions 10 and 14. After a connection has been extended from the operator's position 14 over the trunk line 12 to the operator's position 10, it may obviously be further extended to a desired called substation from the last-mentioned operator's position. The trunk line 12 is a two-way trunk line and, hence, calls may also be forwarded to the operator's position 14 from operator's position 10 located in the exchange A. The arrangement of the trunk circuit apparatus 10a is such that this apparatus may also be used in conjunction with the repeater 16 in routing connections through the automatic switching apparatus provided in the exchange B on calls initiated at a time when the operator's position 14 is not attended. More particularly, if the operator attending the operator's position 10 seizes the trunk circuit apparatus 10a at a time when the operator's position 14 is unattended, this trunk circuit apparatus operates to transmit a seizing pulse of alternating current over the trunk lines 12 and 28 to the repeater 16. The repeater 16 responds to the alternating current seizing pulses by operating to establish a loop circuit extending by way of the trunk lines 29 and 30 to the incoming connector switch 17. Following seizure of the trunk circuit apparatus 10a, the operator initiating the call at the operator's position 10 dials the directory number of the particularly desired substation, the trunk circuit apparatus 10a being arranged to transmit alternating current pulses representing the dialed digits over the trunk lines 12 and 28 to the repeater 16. This repeater functions to convert the received alternating current pulses into corresponding direct current impulses which are transmitted over the trunk lines 29 and 30 to

the incoming connector switch 17. From this point on the connection may be forwarded to a substation line terminating at any one of the exchanges B, C, D and E in the exact manner described previously with reference to calls routed by way of the operator's position 14 and through the incoming connector switch 17. It is to be observed that the toll offering feature of the system is preserved when the calls originate at the operator's position 10 rather than the operator's position 14. Thus, if the operator receives busy tone after dialing the digits of the directory number designating a particular desired substation, she may operate the toll offering switch embodied in the trunk circuit apparatus 10a to cause this apparatus to transmit a supervisory pulse of alternating current over the trunk lines 12 and 28 to the repeater 16. This repeater responds to the alternating current supervisory pulse by unbalancing the loop circuit extending to or through the incoming connector switch 17. From the foregoing description, it will be apparent that when this loop circuit is unbalanced, a connection is established to the busy called line providing the called line terminates at one of the exchanges B, C, D, E and F. Not only is the toll offering feature retained on calls originating at the operator's position 10, but, in addition, the same mode of control, namely, reverse battery control, is utilized in controlling the supervisory lamp provided at the operator's position 10 in association with the trunk line 12. Thus, when a call routed from the operator's position 10 through the repeater 16 and the incoming connector switch 17 to a desired substation is answered, battery is reversed over the loop extending between the incoming connector switch 17 and the repeater 16. Moreover, each time the loop circuit extending to the called substation is thereafter interrupted or recompleted, a corresponding battery reversal over the loop extending between the repeater 16 and the incoming connector switch 17 occurs. The repeater 16 responds to each battery reversal over the last-mentioned loop circuit by operating to transmit a supervisory pulse of alternating current back over the trunk lines 28 and 12 to the trunk circuit apparatus 10a. This apparatus responds to the first received alternating current supervisory pulse by operating to open a point in the circuit for energizing the supervisory lamp individually associated with the trunk line 12. The trunk circuit apparatus 10a further responds to each additional received alternating current supervisory pulse by alternately opening and closing the circuit for energizing the indicated supervisory lamp.

If the connection as routed from the operator's position 10 over the trunk lines 12 and 28 and through the repeater 16 to the incoming connector switch 17 is to be extended to a subscriber's line terminating at the exchange F, the first two digits dialed at the operator's position 10 are the digits designating the trunk line 42 extending to the exchange F. The incoming connector switch 17 responds to the impulses of these digits by operating to seize the trunk line 35 extending to the repeater 18 and to establish a local loop circuit between the repeater 18 and the repeater 16. The repeater 18, in turn, responds to the completion of this loop circuit by marking the trunk line 37' as busy in the bank contacts of the connector switches provided in the exchange B and by completing a loop circuit extending by way of the connected trunk lines 75

41 and 42 to the automatic switching apparatus provided in the exchange F. Following the last-mentioned operation and when the additional digits designating the desired called substation are dialed at the operator's position 10, the repeaters 16 and 18 operate to repeat the dialed impulses over the trunk lines 41 and 42 to the automatic switching apparatus provided in the exchange F. Thus, the connection is forwarded to the desired called substation.

The release of a connection as routed from the operator's position 10 and through the repeater 16 and the incoming connector switch 17 to a called substation is entirely under the control of the operator attending the operator's position 10. Thus, in the case just described of the connection routed to a subscriber's line terminating at the exchange F, when the connection is cleared out at the operator's position 10 the trunk circuit apparatus 10a is released. During the release of this apparatus, a release pulse of alternating current is transmitted therefrom over the trunk lines 12 and 28 to the repeater 16. This repeater responds to the alternating current release pulse by restoring to normal, and, during its release, interrupts the loop circuit extending by way of the trunk lines 28 and 30 through the incoming connector switch 17 to the repeater 18. The repeater 18 now releases and, while restoring to normal, opens the loop circuit extending by way of the trunk lines 41 and 42 to the operated switch train in the exchange F, thereby to initiate the release of this switch train. Also, during its release the repeater 18 functions to remove guarding ground potential from the control conductor of the trunk line 37', thereby to render the trunk line 42 accessible to the connector switches provided in the exchange B. If the connection as routed from the operator's position 10 through the repeater 16 and the incoming connector switch 17 is further extended to a subscriber's line terminating at one of the exchanges B, C, D and E rather than the exchange F, the release of the portion of the switch train following the incoming connector switch 17 is initiated when the loop circuit extending from the repeater 16 to the incoming connector switch 17 is interrupted. The manner in which the portion of the operated switch train following the incoming connector switch 17 is released is substantially similar to the mode of releasing the switch trains described above with reference to calls originating at the operator's position 14.

As explained previously, calls originating at or routed by way of the operator's position 10 and intended for a subscriber's substation associated with a line terminating at the exchange D are normally routed over one of trunk lines 60 in the group including the trunk line 13 directly connecting the operator's position 10 with the automatic switching equipment provided in the exchange D. Thus, when the trunk circuit apparatus 10b is seized by the operator attending the operator's position 10, it operates to transmit a seizing pulse of alternating current over the trunk line 13 to the repeater 72. This repeater, in turn, operates to establish a loop circuit to the associated incoming connector switch 67 and to mark itself as busy in the bank contacts of the local and incoming connector switches having access thereto. After seizing the trunk circuit apparatus 10b, the calling operator dials the directory number of the de-

sired substation and during the dialing operation the trunk circuit apparatus operates to transmit the dialed impulses as alternating current pulses over the trunk line 13 to the repeater 72. The repeater 72 converts the received alternating current pulses into direct current impulses which are transmitted over the established loop circuit to the incoming connector switch 67. This incoming connector switch responds to the first series of impulses by selecting the group of lines including the desired called line. When the second series of impulses is thereafter transmitted to the incoming connector switch 67, this switch operates to select the called line from the selected group of lines and to test the line for the purpose of determining the idle or busy condition thereof. Assuming that the line 75 is the called line and further that this line is idle at the time it is selected by the incoming connector switch 67, ringing current is projected thereover to energize the signal device provided at the called substation T_8 and the usual ring-back tone signal is returned to the telephone station provided at the operator's position 10 to inform the operator that the called substation is being rung. Finally, the ringing operation is arrested and the desired conversational connection between the operator's telephone station and the called substation is completed when the call is answered at the called substation. If the line 75 is busy at the time it is selected by the incoming connector switch 67, the control apparatus of this switch functions to return the usual busy tone signal to the calling operator attending the operator's position 10. The operator may now clear out the connection to initiate the release of the operated switch train, or she may cause a connection to be established to the busy line for the purpose of offering the toll call to the party using the substation T_8 . Assuming that the operator elects to offer the toll call to the subscriber at the called substation T_8 , she momentarily actuates the toll offering switch embodied in the trunk circuit apparatus 10b, whereby this apparatus is caused to transmit a supervisory pulse of alternating current over the trunk line 13 to the repeater 72. The repeater 72 responds to the received alternating current supervisory pulse by operating to unbalance the loop circuit extending therefrom to the incoming connector switch 67. The incoming connector switch 67, in turn, responds to the unbalanced loop circuit condition by operating to establish a bridging connection to the called subscriber's line 75. The calling operator may now converse with the party using the substation T_8 and offer the toll call to this subscriber. If the call is accepted, the parties conversing over the previously established connection including the called line 75 are instructed to hang up, thereby to initiate the release of the previously established connection. During the release of the last-mentioned connection, the called line 75 is marked as idle in the bank contacts of the incoming connector switch 67. The indicated incoming connector switch now operates to project ringing current over the called line 75, thereby to energize the signal device provided at the called substation and to impress ground potential upon the control conductor of the called line for the purpose of guarding this line against seizure by one of the other connector switches having access thereto. When the call is answered at the called sub-

station, the ringing operation is arrested and the desired talking circuit is completed between the called substation and the operator's telephone station located at the operator's position 10. After the connection is fully established to the called substation, the operator supervising the call at the operator's position 10 may extend the connection back to a calling subscriber's substation in the manner conventionally employed in manual office practice. Following the completion of the connection between the calling and called substations, the operator relies upon the supervisory lamp embodied in the trunk circuit apparatus 10b and associated with the trunk line 13 to indicate the condition of the established connection. Thus, if the called subscriber desires to recall the operator attending the operator's position 10, he may do so by operating the switch hook provided at the called substation momentarily to interrupt the loop circuit extending to this substation one or more times. Each time this loop circuit is interrupted, the battery reversing relay embodied in the incoming connector switch 67 operates to reverse battery back over the loop extending to the repeater 72 with the result that this repeater operates to transmit a supervisory pulse of alternating current over the trunk line 13 to the trunk circuit apparatus 10b. The indicated trunk circuit apparatus responds to the received pulse of alternating current by completing the circuit for energizing the supervisory lamp individually associated with the trunk line 13. In a similar manner, each time the loop circuit extending to the called substation is reconnected, the battery reversing relay embodied in the incoming connector switch 67 again reverses battery over the loop circuit extending to the repeater 72 and the control apparatus of this repeater operates to transmit a pulse of alternating current to the trunk circuit apparatus 10b. The last-mentioned apparatus responds to each alternating current pulse resulting from the reconnection of the loop circuit extending to the called substation by operating to open the circuit for energizing the supervisory lamp individually associated with the trunk line 13. Thus, if the loop circuit extending to the called substation is repeatedly interrupted, the indicated supervisory lamp is intermittently energized and the flashing thereof indicates to the operator that she is being recalled by the subscriber at the called substation T_8 . The release of the connection as established to the substation T_8 from the operator's position 10 is under the control of the operator attending this position. Thus, if the called subscriber hangs up to open the loop circuit extending to the called substation before the connection is cleared out at the operator's position 10, the battery reversing relay embodied in the connector switch 67 reverses battery over the loop circuit extending to the repeater 72 and this repeater operates to transmit a final alternating current supervisory pulse over the trunk line 13 to the trunk circuit apparatus 10b. The indicated trunk circuit apparatus now operates to complete the circuit for energizing the supervisory lamp embodied therein and individually associated with the trunk line 13 and the resulting continuous illumination of this lamp indicates to the operator that the connection is ready to be released. When the connection is cleared out at the operator's position 10, the trunk circuit apparatus 10b is released and during its release operates

to transmit a release pulse of alternating current over the trunk line 13 to the repeater 72. The repeater 72 responds to the received pulse of alternating current by restoring to normal and, during its restoration, interrupts the loop circuit extending to the operated incoming connector switch 67. This incoming connector switch now releases and, during its release, removes ground potential from the control conductor of the called line 75, thus rendering this line accessible to the connector switches provided in the exchange D. Following the release of the incoming connector switch 67, the connection as established between the operator's position 10 and the substation T₈ is fully released and the switching equipment utilized in setting up the connection is available for further use.

If the call as initiated at the operator's position 10 and routed through the trunk circuit apparatus 10_b and the repeater 72 to the incoming connector switch 67 is to be extended to a substation, such, for example, as the substation T₄, associated with a line terminating at the exchange C, the operator, after seizing the trunk circuit apparatus 10_b, dials a single digit of one impulse designating the trunk line 65. The incoming connector switch 67 responds to the impulse of the digit by operating to seize the repeater 66 associated with the trunk line 65. The incoming connector switch 67 responds to the impulse of the digit by operating to seize the repeater 66 associated with the trunk line 65. More particularly, when the trunk line extending from the incoming connector switch 67 to the repeater 66 is seized, the indicated incoming connector switch operates to establish a local loop circuit between the two repeaters 72 and 66. When this loop circuit is completed, the repeater 66 operates to transmit a seizing pulse of alternating current over the trunk line 65 to the repeater 57 terminating the distant end of the line 65 in the exchange C. The repeater 57 responds to the received alternating current seizing pulse by operating to establish a loop circuit to its associated incoming connector switch 56 and by impressing ground potential upon the control conductor of the trunk line 64, thereby to guard this trunk line against seizure by one of the incoming connector switches provided in the exchange C. After dialing the digit designating the trunk line 65, the calling operator located at the operator's position 10 continues the dialing operation by dialing the two digits designating the called line 59. The impulses of the final two digits are transmitted as direct current impulses over the local loop circuit extending between the repeaters 72 and 66 to the last-mentioned repeater, which repeater operates to convert the direct current impulses into corresponding alternating current pulses and to transmit the alternating current pulses over the trunk line 65 to the repeater 57. The repeater 57, in turn, reconverts the alternating current pulses into corresponding direct current impulses which are transmitted to the incoming connector switch 56. The incoming connector switch 56, in turn, operates in response to the two series of received impulses by selecting the called line 59. Assuming this line to be idle, the control apparatus embodied in the incoming connector switch 56 operates to project ringing current thereover, thereby to energize the signal device provided at the called substation, and to return the usual ring-back tone signal to the calling operator. When the call is answered at the called substation, the ringing operation is arrested and the desired talking circuit is completed between the calling operator's telephone station and the called substation. On the other hand, if the

5 called line is busy at the time it is selected by the incoming connector switch 56, this switch functions to return busy tone to the calling operator to indicate that the called line is in use. Upon receiving busy tone, the operator may clear 10 out the connection to release the operated switch train or break in upon the previously established connection including the called line to offer the toll call to the party using the substation T₄. More particularly, if the operator momentarily actuates the toll offering switch embodied in the 15 trunk circuit apparatus 10_b, the repeater 72 functions, in the manner previously explained, to unbalance the loop circuit extending through the incoming connector switch 67 to the repeater 66. The repeater 66 responds to the unbalanced loop circuit condition by transmitting a control pulse of alternating current over the trunk line 65 to the repeater 57, causing the last-mentioned repeater to operate and unbalance the loop circuit 20 extending therefrom to the incoming connector switch 56. When the last-mentioned loop circuit is unbalanced, the incoming connector switch 56 operates to establish a bridging connection to the called subscriber's line 59 and thus complete a talking circuit between the substation T₄ and the calling operator's telephone station. The operator may now break in upon the conversation ensuing over the previously established connection and offer the toll call to the party using the substation T₄. If the toll call is accepted, the parties conversing over the previously established connection are instructed to hang up for the purpose of releasing the connection. During the release 25 of the previously established connection, the line 59 is marked as idle in the bank contacts of the incoming connector switch 56 with the result that this switch operates to project ringing current over the line 59 to energize the signal device provided at the called substation. Finally, the ringing operation is terminated and the desired talking circuit is completed when the call is answered at the called substation. On a call of this character, the supervisory lamp embodied in the trunk 30 circuit apparatus 10_b is also relied upon by the operator attending the operator's position 10 to indicate the condition of the connection after it is fully established between the calling and called substations. Here again, the called subscriber may recall the operator by repeatedly interrupting the loop circuit extending to the called substation. In this case, each time the loop circuit extending to the called substation is interrupted, the battery reversing or back bridge relay embodied 35 in the incoming connector switch 56 reverses battery over the loop extending to the repeater 57. This repeater responds to the reversal of battery over the loop circuit extending thereto by operating to transmit a supervisory pulse of alternating current over the trunk line 65 to the repeater 66. The repeater 66, in turn, operates to reverse battery over the local loop circuit extending through the incoming connector switch 67. In a similar manner, each time the loop circuit extending 40 to the called substation is recompleted, the battery reversing relay embodied in the incoming connector switch 56 functions to again reverse battery over the loop extending to the repeater 57 causing this repeater to operate and transmit an additional pulse of alternating current over the trunk line 65 to the repeater 66. The repeater 66, in turn, responds to the received additional pulse of alternating current by reversing battery over the local loop circuit extending through the incoming connector switch 67 to the repeater 72.

Thus, each time the loop circuit extending to the called substation T_4 is interrupted and recompleted at this substation, the repeater 72 is caused to transmit two successive supervisory pulses of alternating current over the trunk line 13 to the trunk circuit apparatus 10_b . The trunk circuit apparatus 10_b responds to the received pulses of alternating current resulting from the interruption of the loop circuit extending to the called substation by operating to complete the circuit for energizing the supervisory lamp individually associated with the trunk line 13 . Conversely, the trunk circuit apparatus 10_b responds to the received alternating current pulses resulting from the recompletion of the loop circuit extending to the called substation by operating to open the circuit for energizing the indicated supervisory lamp. Hence, if the loop circuit extending to the called substation is repeatedly interrupted, the supervisory lamp associated with the trunk line 13 is intermittently energized and flashes to indicate to the operator that she is being recalled by the called subscriber. The release of the connection as established to the called substation T_4 is, like the connection established to the substation T_3 , under the control of the operator attending the operator's position 10 . Thus, if the called subscriber at the substation T_4 hangs up before the connection is cleared out in the operator's position 10 , the incoming connector switch 56 , the repeaters 57 , 66 and 72 and the trunk circuit apparatus 10_b cooperate in the manner just explained to cause the supervisory lamp individually associated with the trunk line 13 to be energized, thus indicating to the operator attending the position 10 that the connection is ready to be released. The manner in which the trunk circuit apparatus 10_b and the repeater 72 are released when the connection is cleared out at the operator's position 10 is exactly the same as described above with reference to the call routed to the substation T_3 . During the release of the repeater 72 , the local loop circuit extending through the incoming connector switch 67 to the repeater 66 is interrupted, whereby the release of the repeater 66 is initiated. During its release, the repeater 66 operates to remove ground potential from the control conductor of the trunk line extending from this repeater to the incoming connector switch 67 , thus initiating the release of the incoming connector switch. Also, during its release, the repeater 66 functions to transmit a release pulse of alternating current over the trunk line 65 to the repeater 57 , whereby the release of the last-mentioned repeater is initiated. During the release of the repeater 57 , ground potential is removed from the control conductor of the trunk line 64 to render the indicated repeater accessible to the incoming connector switches having access thereto and the loop circuit extending to the incoming connector switch 56 is opened. The incoming connector switch 56 now restores and during its restoration removes ground potential from the control conductor of the subscriber's line 59 , whereby this line is also rendered accessible to the connector switches provided in the exchange C and having access thereto. Thus, the connection as established between the operator's telephone station at the position 10 and the called substation T_4 is fully released.

If desired, the connection as forwarded through the automatic switching apparatus provided in the exchange D and over the trunk line 65 to the incoming connector switch 56 , in the manner explained in the preceding paragraph, may further

be extended over one of the trunk lines interconnecting the exchange C and the exchange B and through the automatic switching apparatus provided in the last-mentioned exchange to a subscriber's line terminating at the exchange B , to the operator's position 14 in the exchange B or to a subscriber's line terminating at either of the two exchanges E and F . To this end, the calling operator attending the operator's position 10 , after dialing the digits requisite to the seizure of the trunk line 65 , the repeater 57 and the incoming connector switch 56 , dials an additional digit designating one of the group of trunk lines interconnecting the exchanges B and C . The impulse or impulses of this additional digit is repeated to the incoming connector switch 56 through the repeater chain comprising the repeaters 72 , 66 and 57 , in the manner previously explained, and the indicated incoming connector switch responds thereto by selecting one of the trunk lines in the group of trunk lines including the line 31 . Assuming, for example, that the line 31 is the line selected, the incoming connector switch 56 operates to seize the trunk line 62 extending to the repeater 50 associated with the trunk line 31 . When the line 62 is seized, the incoming connector switch operates to establish a local loop circuit between the two-way repeater 57 and the repeater 50 . When this local loop circuit is completed, the repeater 50 operates to impress ground potential upon the control conductor of the trunk line 62 , thereby to maintain the incoming connector switch 56 operated, and also to transmit a seizing pulse of alternating current over the trunk line 31 to the distant repeater 24 , in the manner previously explained. The last-mentioned repeater responds to the alternating current seizing pulse transmitted thereto by completing a loop circuit to the line circuit 23 , whereby this line circuit is caused to operate to impress ground potential upon the start conductor extending to the distributor 26 and to mark the line 46 as a calling line in the bank contacts of the local finder switches provided in the exchange B . Thus, the operation of the finder portion of an assigned one of the finder-connector links, as, for example, the link 25 , is initiated to seize the line 46 . At this point, it will be observed that the connection resulting from the call initiated at the operator's position 10 is extended to the connector portion of one of the local finder-connector links provided in the exchange B . Assuming, for example, that the link 25 is assigned to the use of the call and operates to seize the calling line 46 , the manner in which the connection may further be extended through this link to one of the subscribers' lines terminating at the exchange B , to the operator's position 14 in the exchange B or to a line terminating at either of the two exchanges E and F , is exactly the same as described previously with reference to the call initiated at the substation T_3 . In this regard, it is pointed out that, after the connection is extended to the local finder-connector link 25 , the five repeaters 72 , 66 , 57 , 50 and 24 cooperate to repeat the impulses of additional digits dialed at the calling operator's position to the connector portion of the link 25 . The character or number of impulses making up the digits transmitted to this link is in no way affected by the other automatic switches included in the established switch train. This is in contrast to the connection described previously with reference to the call initiated at the substation T_4 and routed through the automatic switching apparatus provided in the ex-

change B to the toll operator's position 14 located in the exchange B. In the latter case, the arrangement of the switching selector repeater 51 is such that a connection is only routed to the automatic switching apparatus provided in the exchange B if the first digit 0 of the toll operator's directory number is dialed at the calling substation T4. If any other first digit is dialed at this substation, the switching selector repeater 51 or any of the other similar repeaters operates to release the portion of the switch train which includes the seized automatic switches provided in the exchange B. Thus, a subscriber having a substation associated with a line terminating at the exchange C can only control the automatic switching apparatus provided in the exchange B to cause a connection to be routed to one of the toll operators' positions provided in the exchanges A and B, whereas the operator attending the operator's position 10 may control the automatic switching apparatus provided in the exchange C to establish a connection to a line terminating at this exchange or alternatively may control the apparatus provided in the exchange B to cause a connection to be routed by way of this apparatus to a substation line terminating at any one of the exchanges B, E and F or to the operator's position 14.

The release of a connection as routed from the operator's position 10 through the automatic switching apparatus provided in the exchanges D and C and the local finder-connector link 25 provided in the exchange B to a desired telephone station is primarily under the control of the operator attending the position 10 in the exchange A. More particularly, when the operator clears out the connection at this position, the trunk circuit apparatus 10b, the repeater 72, the incoming connector switch 67, the repeater 66 and the repeater 57 are released in the manner previously explained with reference to the call routed to the substation T4. During the release of the repeater 57, the established local loop circuit extending through the incoming connector switch 56 to the repeater 50 is interrupted. The repeater 50 is now caused to restore and during its restoration removes ground potential from the control conductor of the trunk line 62, thereby to initiate the release of the incoming connector switch 56. During its release, the repeater 50 also operates to transmit a relatively long release pulse of alternating current over the trunk line 37 to the repeater 24. The repeater 24 now starts to release and during its release opens the loop circuit extending by way of the lines 45 and 46 to the local finder-connector link 25. If the connection was routed to a substation associated with a line terminating at the exchange B, the local finder-connector link 25 is released in response to the interruption of the last-mentioned loop circuit and during its release operates to remove ground potential from the control conductor of the line 46, whereby the line circuit 23 is restored to normal. On the other hand, if the connection was routed through the local finder-connector link 25 to the operator's position 14 or to a repeater associated with a trunk line extending to one of the exchanges E or F, the interruption of the loop circuit extending through the local finder-connector link 25 results in the release of the repeater or trunk circuit apparatus terminating the distant end of the trunk line seized by the connector portion of the link. Thus, the release of the seized repeater or trunk circuit apparatus is initiated and,

during its release, holding ground potential is removed from the control conductor of the trunk line seized by the connector portion of the link 25 and over which the connection was routed. Thus, the release of the local finder-connector link 25 is initiated. The manner in which the switching apparatus, if any, following the local finder-connector link 25, is released, is exactly the same as described previously with reference to the calls initiated at the substation T3. Thus, the connection resulting from the call initiated at the operator's position 10 and routed through the automatic switching apparatus provided in the exchange B to a called telephone station is entirely released and the automatic switching equipment utilized in setting up the connection is rendered available for further use.

SECTION 2.—THE APPARATUS PROVIDED AT THE OPERATOR'S POSITION 10 IN THE EXCHANGE A

As indicated previously, the apparatus provided at the toll operator's position 10 in the exchange A includes two identical sets of trunk circuit apparatus 10a and 10b respectively terminating the trunk lines 12 and 13. The trunk circuit apparatus 10a is illustrated in Fig. 4 as comprising a repeating transformer 475 including windings 476 and 477 having line terminals normally connected to the conductors of the trunk line 12. This apparatus further comprises a line connecting jack 482, a calling jack 473, a line signal lamp 493 and a line supervisory lamp 492, each of the two enumerated lamps being individually associated with the trunk line 12. As briefly pointed out above, this trunk circuit apparatus is arranged selectively to be conditioned for ring-down operation in establishing connections between the operator's position 10 and the operator's position 14 on a manual to manual exchange basis and to be utilized as control apparatus in routing connections over the trunk line 12 and through the repeater 16 to an automatic subscriber's substation included in the system at a time when the operator's position 14 is not attended. To this end there is provided a transfer switch 483 of the key-operated, locking type which is so connected and arranged that operation of the switch is effective to condition the control relay equipment of Fig. 4 for either form of operation. When the trunk circuit apparatus 10a is conditioned to operate as a link circuit in routing connections from the operator's position 10 to a called subscriber's substation on a straight automatic to automatic basis, it is necessary that supervisory and switching control pulses of alternating current be transmitted over the trunk line 12 to the distant repeater 16. For the purpose of transmitting such switch control pulses of alternating current over this trunk line there are provided two relays R405 and R410, the first-mentioned of which is operative to connect the conductors of the trunk line 12 to the source of alternating current provided in the exchange A and the last-mentioned of which is a pulsing relay which is arranged to respond to the operation of a calling or impulsing device connected to the calling jack 473. In order to control the relay R410 and the corresponding relays respectively embodied in the other trunk circuits accessible to the operator attending the position 10, there is provided a calling or impulsing device 489 having its control springs connected to the contacts of a calling plug 474, which plug is adapted to be received by the calling jack 473. As briefly explained above, under different circumstances

and at different stages in the operation of the trunk circuit apparatus 10a, it is necessary that three different types of alternating current control pulses be transmitted over the trunk line 12 to the repeater terminating the distant end of this line. Thus, on calls outgoing from the operator's position 10 and routed through the trunk circuit apparatus 10a, it is necessary that a seizing pulse of alternating current be transmitted over the trunk line 12 immediately the indicated trunk circuit apparatus is seized. For this purpose, there are included in the apparatus five relays R460, R445, R430, R440 and R433 which operate in the order named when the apparatus 10a is taken for use and cooperate with the control relay R405 to cause a relatively short seizing pulse of alternating current to be transmitted over the trunk line 12. The duration of a pulse of this character is largely determined by the slow-to-operate characteristics of the two relays R445 and R433. The five enumerated relays also cooperate with the control relay R405 to cause a relatively long release pulse of alternating current to be transmitted over the trunk line 12 when a connection routed by way of the trunk circuit apparatus 10a is cleared out by the operator attending the operator's position 10. The duration of this release pulse is primarily determined by the time required for the pendulum type relay R440 fully to restore after its winding is deenergized. As briefly outlined above, one of the operating features of the present system pertains to the arrangement whereby the toll operators, in setting up connections on an automatic to automatic basis, may cause talking circuits to be established to busy called lines for the purpose of offering toll calls to the parties using the called substations. This feature of the system requires that the operator attending the operator's position 10 be able to cause a control pulse of alternating current to be transmitted over the trunk line 12 to the repeater terminating the distant end of this line. To this end, there are provided in the trunk circuit apparatus 10a two additional relays R415 and R420 which, in cooperation with the slow-to-operate relay R445, the slow-to-release relay R430 and the relay R405 are controllable from the operator's position 10 to cause the indicated alternating current control pulse to be transmitted over the trunk line 12. The duration of a pulse of this character is substantially greater than the duration of the seizing pulse mentioned above and substantially less than the duration of the relatively long alternating current release pulse. To initiate the operation of the enumerated relays to transmit a toll offering alternating current control pulse over the trunk line 12, there is provided at the operator's position 10 a toll offering switch, comprising the contact springs 496, which is arranged to control the differentially wound relay R415 over one of the impulsing leads extending to the calling plug 474. In order to control the line signal lamp 493 and the supervisory lamp 492, there are also included in the trunk circuit apparatus 10a, a pair of two-step relays R450 and R455, a slow-to-operate control relay R465 and an alternating current relay R470, which latter relay is arranged to be energized by alternating current projected over the trunk line 12 from the distant repeater 16. The indicated signal lamps are further partially controlled by the relay R460 and are only utilized in the supervision of connections routed by way of the trunk circuit apparatus and completed on

an automatic to automatic basis. When the trunk circuit apparatus is arranged for ring-down operation in completing connections on a manual to manual exchange basis, the supervisory signals embodied in the operator's cord circuit, not shown, are relied upon to supervise connections established by way of this apparatus.

SECTION 3.—THE APPARATUS PROVIDED IN THE EXCHANGE B

Referring now in greater detail to the apparatus provided in the exchange B and considering first the apparatus provided at the operator's position 14, it is pointed out that the trunk lines incoming to this operator's position are terminated at the contact springs of the transfer switch 800. Thus, the trunk line 12 extending to the exchange B is connected to the movable springs 801 and 804 of the switch 800, whereby it may selectively be connected to the trunk circuit apparatus illustrated in the upper portion of Fig. 6 or to the trunk line 28 extending to the repeater 16. Similarly, the trunk line 36, incoming to the operator's position 14 from the connector switches of the local finder-connector links provided in the exchange B, is terminated at the movable contact springs 807 and 813 of the transfer switch 800, whereby it may selectively be connected to the trunk circuit apparatus illustrated in the lower half of Fig. 6 or to the trunk line 40 which also extends to the repeater 16. Again, the trunk line 38 extending to the incoming connector switch 17 is connected to the movable contact springs 816 and 821 of the transfer switch 800, whereby it may selectively be connected to the trunk circuit apparatus illustrated in the upper half of Fig. 7 or to the trunk line 29 outgoing from the repeater 16. Finally, in the illustrated arrangement, the trunk line 41 by way of which connections are routed through the repeater 16 to and from the exchange F, is connected to the movable contact springs 824 and 827 of the transfer switch 800 so that it may selectively be connected to the trunk circuit apparatus illustrated in the lower half of Fig. 7 or to the trunk line 42 extending to the exchange F. Preferably, the transfer switch 800 is of the well-known turret type and is constructed so that, when once operated to one of its two operating positions, it remains in the operated position until manually operated to the other position. Obviously, a plurality of small switches may, if desired, be used in lieu of the larger switch 800 for performing the individual trunk line switching operations. The operator's telephone station 15 which is provided at the operator's position 14 is illustrated in Fig. 5 as comprising a transmitter 500, a receiver 501 and an induction coil 502 including windings 503, 504 and 505 interconnected with the transmitter 500 and the receiver 501 to form a substation circuit of the well-known anti-side-tone type. More particularly, the receiver 501 is bridged across the winding 504 of the induction coil 502 in series with a condenser 506, the arrangement being such that, during operation of the transmitter 500, substantially equal and opposite induced voltages are developed in the winding 504 due to the coupling between this winding and the windings 503 and 505. Hence, during operation of the transmitter 500, the developed signal currents are not reproduced by the receiver 501. Current for energizing the transmitter 500 is supplied to this transmitter from the exchange battery over a circuit includ-

ing the winding of a retard coil 507. For the purpose of connecting the substation circuit just described with any one of the trunk circuits illustrated in Figs. 6 and 7, there is provided a link line 553 which comprises a pair of line conductors C547 and C548 connected to the line terminals of the induction coil windings 503 and 504 and a conductor C546 included in the circuit for energizing the transmitter 500. This link line also includes a pulse control conductor C549 which is utilized in the transmission of switch control impulses from the operator's telephone station 15 on calls originating at the operator's position 14. More particularly, there is provided a calling or impulsing device 508 including shunt springs 509 arranged to control a slow-to-release shunt relay R540. The calling device 508 also includes a pair of impulsing springs 510 which are connected to transmit switch control impulses over the pulsing leads C550 and C551. As shown in the drawings, the slow-to-release relay R540 is provided with an armature RA541 for effectively short-circuiting the receiver 501 during operation of the calling device 508, thereby to prevent transients produced as an incident of the operation of the calling device 508 from being reproduced as clicks by the indicated receiver.

For the purpose of establishing jumper or link connections between talking circuits established to the operator's position 14 on calls routed to this position and talking circuits routed from the operator's position 14 to the desired called substations, there is also included in the apparatus provided at the operator's position 14 a plurality of link or connecting lines, one of which is indicated at 552. Each such link line has associated therewith a supervisory lamp and a plurality of line signal lamps individually corresponding to the trunk circuits provided at the operator's position 14. Thus, the link line 552 has individually associated therewith a supervisory lamp 511 and a plurality of line signal lamps 649, 679 and 706, which line signal lamps are individually associated with the two trunk circuits shown in Fig. 6 and the lower trunk circuit of Fig. 7. In order to supplement the visual signal provided by the supervisory lamp 511 and the other supervisory lamps individually corresponding to the other link lines, there is provided at the operator's telephone station 15 an audible signal device in the form of a buzzer 535 which is arranged to be controlled by a relay R530. This relay is connected to be energized in series with any one of the supervisory lamps individually associated with the link lines provided at the operator's position 14. The visual signals provided by the line signal lamps associated with the respective link lines are also adapted to be supplemented by the operation of an audible signal device in the form of a second buzzer 525 having an operating circuit controlled by the relay R520. This relay is arranged to be energized in series with any one of the respective line signaling lamps. The arrangement is such that the two audible signaling devices 525 and 535 may be locked out of service by the operator attending the position 14, if the audible signals are not desired. To this end, there is provided a manually operable key controlled switch of the locking type which includes a set of contact springs 513 commonly included in the operating circuits for the two signaling devices 525 and 535. For the purpose of connecting the link line 553 extending to the operator's telephone set to

the respective trunk circuits provided at the operator's position 14, each trunk circuit includes therein a call and answer switch. These four switches for the four trunk circuits illustrated are indicated generally at 619, 666, 764 and 701, respectively. In a similar manner, each of the trunk circuits includes therein a line connecting switch whereby connections may be established to each of the other connecting link lines provided at the operator's position 14. These switches as provided for connecting the four trunk circuits illustrated to the link line 552 are indicated at 607, 658, 757 and 701, respectively. Each of the enumerated switches is of the key operated locking type of which several well-known embodiments are commercially available.

Referring now more particularly to the trunk circuit normally terminating the trunk line 12 interconnecting the exchanges A and B, this circuit comprises a repeating transformer 600 including two windings 601 and 602 having line terminals adapted to be connected to the respective line conductors of any one of the link lines provided at the operator's position. The transformer 600 further comprises a pair of windings 604 and 605 having line terminals normally connected to the conductors of the link line 830 having line conductors connected to the contact springs 802 and 805 of the transfer switch 300. For the purpose of projecting ringing current over the link line 830 and the trunk line 12 on calls originating at the operator's position 14 and completed on a manual to manual exchange basis, there is provided a slow-to-operate ringing relay R645 and a key operated ringing switch 632. The line and supervisory lamps commonly associated with this trunk circuit are arranged to be controlled by the three relays R630, R635 and R640, the first of which is an alternating current relay connected to be energized by ringing current projected over the trunk line 12 and the link line 830. This alternating current relay is arranged to control the normally energized slow-to-release relay R635 and the last-mentioned relay, in turn, directly controls the line signal lamp 649 individual to the trunk circuit apparatus normally terminating the trunk line 12. The relay R640 is provided to insure the energization of the slow-to-release relay R635 when the trunk circuit apparatus is not in use.

The trunk circuit apparatus normally terminating the trunk line 36 extending from the bank contacts of the connector switches embodied in the respective local finder-connector links provided in the exchange B is illustrated in the lower half of Fig. 6 as comprising a repeating transformer 650 and three relays R685, R680 and R695. The transformer 650 includes two windings 651 and 652 having line terminals arranged to be connected to the line conductors of any one of the link lines provided at the operator's position 14. This transformer also includes two additional windings 654 and 655 having line terminals normally connected by way of the conductors of the link line 831 to the contact springs 808 and 814 of the transfer switch 800. Of the three enumerated relays R685, R690 and R695, the relay R685 is in the nature of a line relay and is operative when the trunk line 36 extending to the trunk circuit apparatus is seized. This relay is arranged to control the line signal lamp 679 individual to the trunk circuit apparatus including the same, and also to control the slow-acting hold relay R690. The

last-mentioned relay functions to control the line signal lamp cut-off relay R695 and also the application of ground potential to the control conductor C837 of the link line 831.

Referring now more particularly to the trunk circuit apparatus normally terminating the trunk line 30 extending to the incoming connector switch 17, this apparatus is illustrated in the upper portion of Fig. 7 as comprising a repeating transformer 711, three control relays R780, R790 and R795, and a toll offering switch comprising the contact springs 753. The transformer 711 includes a pair of windings 712 and 713 having line terminals adapted to be connected to the line conductors of any one of the link lines provided at the operator's position 14 through operation of appropriate ones of the connecting switches mentioned above. This transformer also includes an additional pair of windings 715 and 716 having line terminals normally connected over the conductors of the link line 832 to the contact springs 817 and 822 of the transfer switch 800. This trunk circuit is adapted to be utilized only on calls outgoing from the operator's position 14 and, hence, it is unnecessary to provide a line signal lamp in association therewith. The relay equipment embodied in the line circuit is provided solely for the purpose of enabling outgoing calls to be routed through the incoming connector switch 17 to the desired substation and the resulting connection to be properly supervised. Thus, the relay R780 is arranged to operate in response to operation of the calling device 508 provided at the operator's telephone station 155 to connect the line conductors of the link line 832 to the pulsing leads C550 and C551, whereby switch control impulses may be transmitted over the link line 832 and the trunk line 30 to the incoming connector switch 17. The relay R795 is in the nature of a line relay in that it is adapted to respond to operation of any one of the connecting switches embodied in the trunk circuit apparatus to complete a loop circuit to the associated incoming connector switch 17. The relay R790 is a back bridge relay of the electro-polarized type and is provided for the purpose of controlling the supervisory lamp associated with any one of the link lines, as, for example, the line 552 utilized in completing a connection between two of the substations embodied in the system. The toll offering switch comprising the springs 753 is provided for the purpose of impressing ground potential upon the lower line conductor of the link line 832, thereby to unbalance an established loop circuit extending to the incoming connector switch 17.

The trunk circuit normally terminating the trunk line 42 extending to the exchange F is illustrated in the lower portion of Fig. 7 as comprising a repeating transformer 715 and five control relays R730, R740, R745, R750 and R755. As shown, the transformer 715 includes a pair of windings 716 and 717 having line terminals adapted to be connected to the line conductors of any one of the link lines provided at the operator's position 14 in response to operation of appropriate ones of the line connecting switches embodied in the indicated trunk circuit. The transformer 715 also includes a pair of additional windings 719 and 721 having line terminals normally connected by way of the conductors of the link line 833 to the contact springs 825 and 828 of the transfer switch 803. This trunk circuit is arranged to be used in completing and supervising calls routed to and from the operator's

position 14 over the trunk line 42. On calls incoming to the operator's position over the indicated trunk line, the trunk circuit apparatus is arranged for ring-down operation. More particularly, the relay R750 is an alternating current relay and is connected to be energized by ringing current projected over the link line 42 from the automatic switching apparatus provided in the exchange F. This alternating current relay is arranged to control the normally energized slow-to-release relay R755, which latter relay, in turn, directly controls the line signal lamp 706 individually associated with the trunk circuit apparatus under consideration. The relay R745 is in the nature of a line relay in that it is operative, under the control of the line connecting switches embodied in the trunk circuit, to establish a loop circuit including the trunk line 42 to the automatic switching equipment provided in the exchange F. This relay is also arranged to insure the energization of the slow-to-release relay R755 during intervals when the trunk circuit is not in use. The relay R730 corresponds to the relay R780 described above, in that it is provided for the purpose of connecting the line conductors of the link line 833 to the pulsing leads C550 and C551. Finally, the relay R740 is an electropolarized back bridge relay and is provided for the purpose of controlling the supervisory lamp individually associated with the one of the link lines utilized in establishing a jumper connection between two talking circuits extending to the operator's position 14.

Referring now more particularly to the automatic switching apparatus provided in the exchange B and considering first the two-way repeaters 16 and 24, it is pointed out that these two repeaters are of identical arrangement and that corresponding elements thereof are identified by reference numerals having the same tens and units digits. Considering the repeater 16 by way of example, this repeater is illustrated in Figs. 10 and 11 as comprising a repeating transformer 1173 including a pair of windings 1174 and 1175 having line terminals adapted to be connected to the line conductors of the trunk line 40, the line conductors of the trunk line 44, or the line conductors of the trunk line 29 depending upon the point of origin of a call routed through the repeater. The transformer 1173 also comprises a second pair of windings 1178 and 1179 having line terminals normally connected to the conductors of the trunk line 28 extending to the operator's position 14. As indicated previously, the control apparatus embodied in the repeater 16 is arranged to transmit and respond to control or supervisory pulses of alternating current of three different types, distinguished only by the extent or duration thereof. The repeater is also arranged to convert received alternating current switch control pulses transmitted thereto over the trunk line 12 into corresponding direct current impulses which are transmitted over the trunk line 29. More particularly, the relay equipment embodied in the repeater 16 comprises an alternating current relay R1115 which is connected to respond to each pulse of alternating current transmitted over the trunk line 12 from the operator's position 10 when this trunk line is connected to the trunk line 28 extending to the repeater 16. The relay equipment embodied in the indicated repeater further comprises a plurality of relays R1050, R1060, R1100, R1105, R1110, R1130, R1150, R1160, R1165 and R1170, all of which are arranged to be controlled

by the alternating current pulse responsive relay R1115 during the operation of the repeater to extend a connection routed thereto over the trunk line 12 through the incoming connector switch 17 to a desired called substation. More particularly, the relay R1050 is of the two-step type and is arranged partially to operate in response to the first operation of the relay R1115 and to complete its operation when the relay R1115 subsequently restores. The relay R1130 is arranged to operate in response to the operation of the two-step relay R1050 and functions to control the operation of the three relays R1100, R1105 and R1110. These three relays are arranged to operate in a cyclic manner and function to control the operation of a stepping switch generally indicated at 1070. This stepping switch is arranged to perform a variety of functions, among which are its operation to initiate the release of the repeater when a connection routed by way thereof is released and its operation to initiate the release of the repeater in the event at least one pulse of alternating current, following an alternating current seizing pulse, is not transmitted thereto within a predetermined time interval. More particularly, there is provided a slow-to-release relay R1045 which is arranged to release the repeater 16 in response to the operation of the stepping switch 1070 to a predetermined one of its plurality of off-normal positions. The stepping switch 1070 is of the well-known minor type and comprises two sets of contacts, two wipers electrically connected together and indicated as a single wiper 1071, an operating magnet 1072 for driving the wipers over the contacts of their respective associated contact sets, a release magnet 1073, and a set of off-normal springs 1074 for controlling the energization of the release magnet.

The arrangement of the repeater 16 is such that, after the repeater is seized, the relay R1115 follows the alternating current switch control pulses transmitted thereto over the trunk line 12 in response to operation of the calling device 489, and the two relays R1160 and R1170 respond to the operation of the relay R1115 to repeat the pulses as direct current impulses over the outgoing trunk line 29 to the incoming connector switch 17. More particularly, the two relays R1160 and R1170 comprise an impulse correcting network arranged to compensate any distortion of the alternating current impulses. During impulsion, the slow-to-release relay R1165 and the relay R1140 cooperate to cause the deenergization of the relay R1130 at the beginning of the first pulse of the first pulse train transmitted to the repeater 16 after the seizure thereof, whereby the cyclic operation of the three relays R1100, R1105 and R1110 and the operation of the switch 1070 are arrested. The arrangement is such that the release circuit of the switch 1070 is closed to cause the wiper 1071 to be returned to its normal or home position each time the cyclic operation of the three relays is arrested. During impulsion, the slow-acting relay R1060 functions to reduce the impedance of the loop circuit extending to the operated incoming connector switch, whereby the repeated impulses are more effectively transmitted to this switch. As briefly pointed out above, after a connection has been routed through the incoming connector switch 17 to a busy called line, it is necessary that the loop circuit incoming to this switch be unbalanced if a talking circuit to the called line is to be established for the

purpose of offering the call to the called subscriber. To this end, the relays R1115, R1165 and R1170 are arranged to respond to a control pulse of alternating current transmitted over the line 12 to the repeater 16 and function to impress ground potential upon one side of the indicated loop circuit, thereby to unbalance the circuit. Although the operation of the relay R1130, the cyclically operating relays R1100, R1105 and R1110 and the stepping switch 1070 is initiated at this time, the resulting operation is without effect and the indicated elements are restored to normal when the control pulse is ended. For the purpose of transmitting alternating current control pulses from the repeater 16 over the trunk line 28, there is provided therein a relay R1140. After a connection routed through the repeater 16 is completed, this relay, as controlled by the cyclically operating relays R1100, R1105 and R1110, functions to transmit control pulses of alternating current over the trunk lines 28 and 12 to the trunk circuit apparatus 10a for the purpose of supervising the established connection. Under the conditions stated, the three enumerated cyclically operating relays are arranged to be controlled by an electropolarized back bridge relay R1065, which relay is connected to respond to reversals of battery over an established loop circuit including the trunk line 28. In order to prevent alternating current from being transmitted over any one of the trunk lines 29, 40 and 44, there is also provided a slow-acting relay R1120 which operates to disconnect the line terminals of the transformer windings 1178 and 1179 from the conductors of the trunk line 28 each time the alternating current pulse control relay R1140 is caused to operate.

The last-mentioned relay, namely, the relay R1140, is also utilized to cause seizing, supervisory and release pulses of alternating current to be transmitted over the trunk line 28 on calls routed to the repeater 16 over either of the trunk lines 40 and 44 incoming to this repeater. More particularly, there are provided line and hold relays R1005 and R1000, respectively, which are successively operated when the repeater 16 is seized over one of the indicated trunk lines. A control relay R1030 is also provided which is arranged to respond to the operation of the hold relay R1000 and functions to initiate the cyclic operation of the three relays R1100, R1105 and R1110, thereby to cause the relays R1120 and R1140 to operate and transmit the desired seizing pulse of alternating current over the trunk line 28. During the release of the connection as routed through the repeater 16 in this direction, the alternating current relay R1115, in cooperation with the relays R1130, R1045 and R1050, the cyclically operating relays R1100, R1105 and R1110, and the stepping switch 1070, operates to cause the release of the repeater when the connection is cleared out at the operator's position 10 in the exchange A.

The control apparatus embodied in the repeater 16 further comprises three additional relays R1012, R1020 and R1040 which are arranged to respond to the operation of the relay R1115 resulting from supervisory pulses of alternating current transmitted to this repeater. The first of these three relays is a battery reversing relay operative to reverse battery over the conductors of the trunk line 40 and the remaining two thereof are provided for controlling the relay R1012. In the particular arrangement of the repeater 16, these relays are not utilized for any control func-

tions, although the presence thereof in no way adversely affects the operation of the repeater. The repeater control apparatus also includes two additional differentially wound relays R1010 and R1024 which are provided for causing a toll offering control pulse of alternating current to be transmitted over the trunk line 28 and are not used in the particular application indicated for the repeater 16. The relays corresponding to the five relays R1010, R1012, R1020, R1024 and R1040 and provided in the repeaters 24 and 50, for example, are utilized in the completion and supervision of connections routed by way of these repeaters. Although the five enumerated relays are not used in the repeater 16, by providing a repeater of universal design for different applications, the unit cost of construction of a number of such repeaters is lowered. In the repeater 24 illustrated in Figs. 17 and 18, the relay R1712, which corresponds to the relay R1012 of the repeater 16, is arranged to reverse battery over the trunk line 32 in response to control pulses of alternating current transmitted to the repeater 24 over the trunk line 31. This battery reversing relay is under the control of the two relays R1720 and R1740 which respectively correspond to the relays R1020 and R1040 provided in the repeater 16. Each of the two relays R1712 and R1720 is of the two-step type, while the relay R1740 is of the slow-to-operate type. The differentially wound relay R1710, which corresponds to the relay R1010 of the repeater 16, is arranged to respond to an unbalanced condition of the loop circuit extending to the repeater 24 to cause the relay R1840 to operate and transmit a control pulse of alternating current over the trunk line 31 to the distant repeater 50. Operation of the cyclically operating relays R1800, R1805, and R1810 and of the stepping switch 1770 is also initiated when the toll offering relay R1710 is caused to operate, the duration of the operating current control pulses being measured by the operation of the stepping switch 1770. More particularly, the pulse is terminated in response to the restoration of the relay R1724 which occurs when the wiper 1771 of the switch 1770 is operated to a predetermined off-normal position.

Referring now more particularly to the line circuits individually associated with the subscribers' lines terminating at the exchange B and considering the line circuit shown in Fig. 22 in association with the line 33 as exemplary of the form of line circuit used in conjunction with lines of the single party type, it will be noted that this line circuit comprises the usual line, cut-off and lockout relays R2250, R2260 and R2255, respectively, of which the last-mentioned relay is of the slow-acting type. This line circuit also comprises a call metering device which is operative to register calls initiated at the substation T₃ individually associated with the line 33. This call metering device is indicated as comprising an operating magnet 2270 having an armature arranged to control an operating pawl 2271 associated with a ratchet wheel 2212 which is arranged to drive the register cylinder of the device. The line circuits individually associated with the trunk lines terminating in the bank contacts of the local finder switches provided in the exchange B are quite similar in arrangement to the line circuit associated with the subscriber's line 33 and described immediately above. Thus, the line circuit 23 associated with the link line 46 and utilized on calls routed over the trunk line 31 to the repeater 24, is shown in Fig. 23 as comprising

the usual line, cut-off and lockout relays R2300, R2320 and R2310, respectively. The line circuits individually associated with the subscribers' lines of the duplex type are somewhat different in character from those terminating lines of the single party type. Thus, the line circuit shown in Fig. 21 in association with the duplex line 34 comprises a line relay R2160, a cut-off relay R2120, a slow-acting lockout relay R2130, two additional relays R2140 and R2150 arranged to be controlled by the line relay R2160, and call registering or metering devices individually corresponding to the two substations associated with the line 34. The line relay R2160 is of the differentially wound type and is so connected and arranged that it remains operated for the duration of calls initiated at one of the two substations associated with the line 34 and remains in its restored position for the duration of calls initiated at the other of the two substations. The relay R2150 is provided for the purpose of selectively connecting the operating magnets 2175 and 2176, respectively embodied in the calling metering devices respectively corresponding to the substations T₁ and T₂, to be energized in response to the application of booster battery potential to the control conductor C2178 of the line 34. The device embodying the operating magnet 2175 is arranged to register calls initiated at the substation T₁ while the device including the operating magnet 2176 is arranged to register calls initiated at the substation T₂, all in the manner explained with particularity hereinafter.

The arrangement of the substation apparatus individually provided at the substations of the single party type is entirely conventional and somewhat different from that of the apparatus provided at the substations associated with subscribers' lines of the duplex type. For this reason, the substation apparatus provided at the substation T₃ in association with the line 33 has been only diagrammatically illustrated, whereas the apparatus provided at each of the substations T₁ and T₂ associated with the duplex line 34 has been shown in detail. The apparatus provided at the substation T₁ comprises a transmitter 2169, a receiver 2168 and a hook switch 2167 for operatively connecting the substation apparatus to the line 34. The apparatus provided at this substation further comprises a calling or impulsing device 2185 and a signal device in the form of a ringer 2180 normally connected in series with a condenser 2181 between the line conductor C1386 and ground. Also provided at this substation is a slow-to-release lock-out relay R2100 having its winding bridged by an audio frequency by-pass condenser 2104 and being utilized to lock the associated substation equipment out of service when the apparatus provided at the substation T₂ is being used. In a similar manner, the equipment provided at the substation T₂ comprises a transmitter 2173, a receiver 2174, and a hook switch including a receiver supporting arm 2172 for operatively connecting the apparatus to the line 34. The equipment provided at this substation further comprises a calling device 2184, a ringer 2182 connected in series with a condenser 2183 between the line conductor C1384 and ground, and a slow-to-release lockout relay R2110 having its winding bridged by an audio frequency by-pass condenser 2114. This relay, like the relay R2100, is provided for the purpose of locking the apparatus provided at the substation T₂ out of service when the substation equipment located at the substation T₁ is being used.

Referring now more particularly to the incoming connector switch 17 illustrated in Figs. 12 and 13, this switch comprises a switching mechanism 1370 of the well-known Strowger type having embodied therein a plurality of bank contacts arranged in levels, wipers 1371 to 1374, inclusive, adapted to traverse and engage the contacts of the associated contact field, a vertical magnet 1256 for elevating the enumerated wipers to a position opposite a desired level, a rotary magnet 1356 for rotating the wipers over the contacts of a selected level and into engagement with a set of contacts terminating a desired line, and a release magnet 1208 for returning the wipers to normal during the release of the switch. This switching mechanism also includes a plurality of sets of off-normal springs indicated at 1207, 1216, 1255, 1257, 1397 and 1398, respectively, which are arranged to perform various control functions described in detail hereinafter. The relay equipment embodied in the incoming connector switch 17 comprises a line relay R1235 a slow-acting hold relay R1240, a slow-acting pulse circuit control relay R1245, and a slave relay R1250 under the control of the series relay R1245 and arranged to control the application of dial tone voltage to the conductors of the trunk line 30. Dial tone voltage is derived through the windings of a transformer 1258 having its primary winding connected to a source of alternating current, not shown. The relay equipment embodied in the connector switch 17 further comprises a busy test relay R1320 which is operative to determine the idle or busy condition of a selected called line and a slow-to-operate line switching relay R1360 which is operative to initiate the ringing operation when a selected called line is tested and found to be idle. For the purpose of controlling the operating and holding circuits for the busy test and line switching relays R1320 and R1360, there are provided three pulse responsive relays R1335, R1340 and R1350, all of which are arranged to operate at the beginning of each series of impulses transmitted to the incoming connector switch 17 and to remain operated until shortly after each impulse series is ended. There is also provided a control relay R1310 which is operative to arrest the ringing operation and to complete a connection to the desired called line when a connection as routed to the line is answered at the called substation. The last-mentioned relay is a slave to a slow-acting ring cut-off relay R1300. After a connection routed through the incoming connector switch is completed, supervision thereof is maintained through the provision of two relays R1217 and R1220, the first of which is arranged to be energized over an established loop circuit extending to a called substation in series with the line balancing impedance element 1219 and is arranged to control the relay R1220. The last-mentioned relay is provided for the purpose of reversing battery over the conductors of the trunk line 30 in response to the completion or interruption of the loop circuit extending to a selected called substation. As indicated previously, the incoming connector switch 17 has access to one or more groups of trunk lines and is arranged for automatic trunk hunting on certain levels. To provide this service, there is included in the switch a relay R1330 which, in cooperation with the busy test relay R1320 and the three impulse responsive control relays R1335, R1340 and R1350, functions to control the rotary magnet 1356 of the switching mechanism 1370 during a trunk hunting operation. The control

apparatus of the incoming connector switch 17 is arranged to establish an uninterrupted metallic circuit between the trunk line incoming thereto and the selected trunk line outgoing therefrom, on a trunk call of the character indicated. To this end, there is provided a switching-through relay R1200 which is arranged to operate following the selection of an idle trunk line of a selected trunk line group. For the purpose of establishing a toll offering connection to a busy called line selected by the incoming connector switch 17, there are also embodied in this switch two additional relays R1230 and R1210, the first of which is of the differentially wound type and is arranged to operate in response to an unbalanced condition of an established loop circuit extending to the switch 17. These two relays, in cooperation with the busy test relay R1320, not only function to cause the desired toll offering connection to be established to a selected busy called line but, in addition, function to cause the called substation to be signaled and the desired talking circuit thereto to be completed following the release of the previously established connection extending to the called substation.

As outlined previously, the subscribers' lines to which the incoming connector switch 17 has access are of three different types, namely, single party lines, lines of the duplex type and lines of the multiplex type. In the selection of a desired substation associated with a selected line of the multiplex type, it is necessary that one series of impulses dialed at the calling telephone station be transmitted to the station selecting apparatus associated with the selected called line. In order to adapt the incoming connector switch 17 to operate in this manner, the switching mechanism 1370 is provided with an extra bank contact field section, the contacts of which are adapted to be traversed by the extra control wiper 1374, and the relay R1304 is provided in the relay equipment of the switch. This relay is arranged to be controlled over a circuit including the indicated extra control wiper and functions to condition the remaining relay apparatus to repeat the impulses of a final digit dialed at the calling telephone station as negative battery pulses over the positive side of a selected line of the multiplex type.

Referring now more particularly to the repeater 20 terminating one end of the trunk line 31' interconnecting the exchanges B and E, this repeater is illustrated in Fig. 16 as comprising a repeating transformer 1670 including windings 1671 and 1672 having line terminals normally connected to the line conductors of the trunk line 38 extending to the bank contacts of the local connector switches provided in the exchange B and also connected to the line conductors of the trunk line 31' extending to the bank contacts of the incoming connector switch 17 described in the preceding paragraph. The transformer 1670 further comprises two additional windings 1673 and 1674 having line terminals adapted to be connected to the line conductors of the trunk line 31'. The control apparatus embodied in the repeater 20 includes a line relay R1655, a slow-acting hold relay R1660 and a slow-to-release line switching relay R1665. There is also included in the indicated relay equipment an electropolarized back bridge relay R1640 which is arranged to respond to reversals in the direction of current flow over a loop circuit established by way of the trunk line 31'. This back bridge relay is arranged to control a battery re-

versing relay R1620 which is provided for the purpose of reversing battery over the line conductors of the trunk line 31 without affecting the direction of current flow or polarity of the voltage impressed upon the line conductors of the trunk line 38. The relay R1620, in cooperation with two additional relays R1645 and R1650, also functions to control the application of booster battery potential to the control conductor C1686 of the trunk line 38. For the purpose of unbalancing an established loop circuit extending by way of the trunk line 31' to the automatic switching apparatus provided in the exchange E, thereby to cause a toll offering connection to be established to a selected busy line on a toll call routed through the repeater 20, there is also provided in this repeater a differentially wound toll offering relay R1630 which is arranged to operate in response to an unbalanced condition of a loop circuit established to this repeater and including the trunk line 31.

The repeater 18 associated with the trunk line 41 and illustrated in Fig. 14 is substantially similar to the repeater 20 described in the preceding paragraph. Thus, the repeater 18 comprises a repeating transformer 1450 including a pair of windings 1453 and 1454 having line terminals normally connected to the line conductors of the trunk lines 35 and 37'. The transformer 1450 also includes two additional windings 1451 and 1452 having line terminals adapted to be connected to the line conductors of the trunk line 41. The relay equipment embodied in this repeater comprises a line relay R1430, a slow-acting hold relay R1405, a slow-to-release line switching relay R1400, an electropolarized back bridge relay R1420 and a battery reversing relay R1440. This battery reversing relay is arranged so that it is only operative to reverse battery over the trunk line 35 extending to the bank contacts of the incoming connector switch 17. The relay equipment embodied in the repeater 18 also includes a differentially wound toll offering relay R1435 which corresponds to the relay R1630 of the repeater 20, and two additional relays R1410 and R1415 which, in conjunction with the back bridge relay R1420 and the battery reversing relay R1440, are operative to control the application of booster battery potential to the control conductor C1461 of the trunk line 37' extending to the bank contacts of the local connector switches provided in the exchange B.

The trunk circuit apparatus 19 which terminates the trunk line 43 outgoing from the repeater 18 is operative to select either of the two trunk lines 44 and 44' and is illustrated in Fig. 15 as comprising an alternating current line relay R1500, a slow-acting hold relay R1510, and a ring cut-off control relay R1520. Also embodied in this apparatus are a pair of trunk selecting relays R1530 and R1540 which jointly control the selection of an idle one of the trunk lines 44 and 44' outgoing from the trunk circuit 19. The relay R1520, which is described as a ring cut-off control relay, is also arranged to control the connection of the busy tone current source provided in the exchange B to the conductors of the trunk line 43, this relay being arranged to operate only in the event one of the trunk lines 44 and 44' is idle at the time the apparatus is seized and a loop circuit by way of the idle trunk line is established to the repeater associated therewith.

Referring now more particularly to the local finder-connector link 25 illustrated in Figs. 19

5 20, the finder portion of this link comprises a rotary finder switch 2070 at which the subscribers' lines extending to the exchange B terminate. This switch includes three sets of bank contacts, wipers 2071, 2072 and 2073, respectively associated with the contact sets, and an operating magnet 2056 for driving the enumerated wipers over the contacts of their respective associated sets. The connector end of the link comprises a Strowger switching mechanism 1900 having a plurality of contacts arranged in levels in the usual manner, wipers 1901 to 1904, inclusive, a vertical magnet 2008 for elevating the wipers to a position opposite a selected level of contacts, a rotary magnet 1974 for rotating the wipers over the contacts of a selected level and into engagement with a set of contacts terminating a desired line, and a release magnet 2033 for returning the enumerated wipers to their respective home positions during the release of the link. The switching mechanism 1900 also includes a plurality of sets of off-normal springs 1997, 2017 and 2034 which perform various control operations described in detail hereinafter. Two additional sets of off-normal springs, one of which is indicated as comprising the springs 2091, 2092 and 2093 and the second of which is indicated as including the springs 2016, 2016' and 2017', are also provided for performing additional control functions referred to in detail hereinafter. The relay network embodied in the link circuit includes the usual line and hold relays R2035 and R2010, respectively, a slow-acting pulse circuit control relay R2005, and a slave relay R2000 which is under the control of the relay R2005 and functions to control the application of dial tone signals to calling lines and also the operation of the ringing and tone apparatus associated with the respective links. For the purpose of connecting the conductors of a selected calling line through to the line terminals of the line relay R2035, there is provided a line switching relay R2050 which is operative when the wipers of the finder switch 2070 are rotated into engagement with the contacts terminating the conductors of a calling line. The relay network further comprises a slow-acting series relay R1930, a slow-acting control relay R1920, and a slave relay R1925 under the control of the relay R1920, all of which are arranged to operate in response to operation of the line relay R2035 during impulsion. The three enumerated relays function to control the respective operating circuits for the busy test and line switching relays indicated at R1940 and R1910, respectively. The line switching relay R1910 is of the slow-to-operate type and functions to project ringing current over a selected idle line shortly after the operation of the switching mechanism 1900 to select a desired line is completed. In order to arrest the ringing operation and to complete the desired talking circuit to the called line when the call is answered at the called substation, there is also provided in the link circuit apparatus a slow-acting ring cut-off relay R1970 which is arranged to control the operation of a slave relay R1950, the last-mentioned relay, in turn, being connected and arranged to perform the actual line switching and ring cut-off operations. In order to provide for the application of booster battery potential to the control conductor of a selected calling line, thereby to control the operation of the call registering device associated with the calling substation, there is also embodied in the link circuit apparatus a slow-to-release control relay

R2030, the operation of which is under the control of a back bridge relay R2020. More particularly, the back bridge relay 2020, which operates only when a call routed to a called line is answered at the desired called substation, is operative to impress booster battery potential upon the control conductor of a calling line and the slow-to-release relay R2030 is operative to determine the period during which booster battery potential is maintained upon the control conductor of the calling line.

As indicated previously, the connector switches embodied in the respective local finder-connector links provided in the exchange B have access to one or more groups of trunk lines and each thereof is arranged for automatic trunk hunting in order to facilitate the selection of an idle trunk line in a selected group. To this end there is provided in the link circuit of the finder-connector link 25 a control relay R1935 which cooperates with the three relays R1920, R1925 and R1930 and the busy test relay R1940 to cause the rotary magnet 1974 to drive the wipers of the switching mechanism 1900 until an idle trunk line of the selected trunk line group is found. On a trunk call of the character indicated, the link circuit apparatus is arranged to provide an uninterrupted metallic circuit between the conductors of a calling line and the line conductors of the selected trunk line. Such a circuit is established through the provision of a switching-through relay R2040 which is arranged to operate only on calls routed to one of the trunk lines terminating at the connector end of the link. In order to adapt the link circuit apparatus of the finder-connector link 25 for use in controlling the station selecting apparatus associated with a selected calling line of the multiplex type, the switching mechanism 1900 is provided with an extra bank contact field section, the contacts of which are adapted to be engaged by the extra control wiper 1903; and a relay R1960, arranged to be energized over a circuit including the extra control wiper 1903, is embodied in the link circuit apparatus. This relay is arranged to operate only on calls routed to a subscriber's line of the multiplex type and functions to condition the link circuit apparatus embodied in the link 25 to repeat the impulses of a final digit dialed at a calling substation as negative battery pulses over the positive side of the selected called line, whereby the station selecting apparatus associated with the called line is caused to operate to select the desired called substation. For the purpose of forcibly releasing the link 25 in those instances when the link may be seized and no switch control pulses are transmitted thereto, there is provided in the link circuit apparatus a pair of bimetallic or thermal control relays indicated at 2058 and 2062, respectively. These two thermal relays are operative to cause the link to be released in any case where the link is seized and no switch control impulses are transmitted thereto within a predetermined time interval.

As pointed out previously, idle ones of the local finder-connector links, including the link 25 described in the immediately preceding paragraph, are successively assigned to the use of successive calling lines through the operation of the distributor 26 illustrated in Fig. 22. This distributor comprises a rotary switch 2200 and control apparatus including a plurality of relays R2210, R2215, R2220, R2225, R2230, R2235, R2240 and R2245. More particularly, the rotary switch 2200 comprises four sets of bank contacts,

5 wipers 2201 to 2204 respectively associated with the contact sets, and an operating magnet 2205 for driving the enumerated wipers over the contacts of their respective associated contact sets. Each position of the enumerated wipers corresponds to one of the associated finder-connector links and, with the wipers standing in any given position, the control apparatus of the distributor is operative to cause the finder portion of the selected link to operate and seize a calling one of the subscribers' lines. More particularly, the relay R2230 is a start relay which is operative in response to the initiation of a call on any one of the subscribers' lines, the relay R2240 is a slow-acting control relay, and the relay R2245 is a combined pulsing and line test relay, this latter relay being arranged to cooperate with the operating magnet of the finder switch embodied in an assigned link to cause the finder switch to search for and seize a calling line. The two relays R2215 and R2220 are provided for purpose of causing the distributor to assign a second link to the use of a calling line in the event a first assigned link fails to find the calling line within a predetermined time interval. The relay R2225 is an all-links-busy relay and is provided for the purpose of preventing the distributor switch 2200 from operating in an attempt to select an idle one of the links at a time when all of the links are busy. This relay also functions to open the operating circuit for the start relay R2230 during those times when all of the links are busy. Finally, the slow-to-release relay R2210 is provided for the purpose of controlling a device, not shown, for registering the number of calls routed through the various local finder-connector links.

SECTION 4.—THE APPARATUS PROVIDED IN THE EXCHANGE C

Referring now more particularly to the details of the automatic switching apparatus provided in the exchange C and considering first the repeaters 50 and 57, it is pointed out that each of these repeaters is in all respects identical with the repeater 16 shown in Figs. 10 and 11 and the repeater 24 illustrated in Figs. 17 and 18. In view of the foregoing description with reference to the two last-mentioned repeaters and the following description of the operation of the repeater 50, it is deemed unnecessary to consider the apparatus of this repeater in detail other than to point out that the repeating transformer 2615 corresponds to the repeating transformer 1173 of the repeater 16 and that the relays R2600, R2605, R2610, R2620, R2630, R2640, R2645, R2650, R2655, R2660, R2670, R2700, R2705, R2710, R2720, R2725, R2730, R2740, R2750, R2760, R2770, R2775 and R2780 respectively correspond to the relays R1170, R1165, R1160, R1150, R1140, R1130, R1120, R1115, R1110, R1105, R1100, R1065, R1060, R1050, R1045, R1040, R1030, R1024, R1020, R1012, R1010, R1005 and R1000, in the order named, of the repeater 16. Also, the stepping switch 2785 embodied in the repeater 50 is provided for the same purpose and performs the same functions as the corresponding stepping switch 1070 embodied in the repeater 16.

The incoming connector switches 53 and 56 individually associated with the repeaters 50 and 57, respectively, are somewhat similar to the incoming connector switch 17 provided in the exchange B and described previously, but differ therefrom in that a different form of switching mechanism is used. More particularly, the incoming connector switch 53 is illustrated in Figs.

31 and 32 as comprising a rotary switch 3250 at which the lines extending to the exchange C are terminated. The switch 3250 comprises six levels of bank contacts, wipers 3251 to 3256, inclusive, respectively associated with the contact levels, and an operating magnet 3257 for driving the enumerated wipers over the contacts of their respective associated contact sets. The control apparatus embodied in the incoming connector switch 53 comprises the usual line and hold relays indicated at R3125 and R3130, respectively, a slave relay R3140 under the control of the slow-acting hold relay R3130, a slow-to-release busy test relay R3200, a slow-to-operate line switching relay R3240, a slow-acting ring cut-off relay R3230, and a slave relay R3235 controlled by the ring cut-off relay R3230. There are also provided three additional relays R3160, R3155 and R3170 which operate during impulsive and are arranged to control the respective operating and holding circuits for the busy test and line switching relays R3200 and R3240, respectively. For the purpose of supervising connections established by way of the incoming connector switch 53, there is also provided therein a battery reversing relay R3110 which is adapted to be energized in series with a line balancing impedance element 3216 when a call is routed through the incoming connector switch 53 is answered at a selected called substation. The switch 53 is arranged for switching-through operation on calls routed by way thereof to the trunk line 64. To this end there is provided a switching-through relay R3100 which is arranged to operate only when the series of impulses designating the trunk line 64 is transmitted to the switch 53. For the purpose of causing the switch to establish toll offering connections to selected busy called lines, there are provided in the control apparatus two additional relays R3120 and R3210. The first of the two last-mentioned relays is of the differentially wound type and responds to an unbalanced condition of an established loop circuit extending to the incoming connector switch 53 by operating to cause the operation of the line switching relay R3210. The last-mentioned relay, in turn, functions to cause the desired toll offering connection to be established to the selected called line.

As pointed out previously, the subscribers' lines extending to the exchange C are, like the lines extending to the exchange B, divided into three classes, namely, single party lines, lines of the duplex type, and lines of the multiplex type having station selecting apparatus individually associated therewith. In order to adapt the operation of the incoming connector switch 53 for use in controlling the station selecting apparatus associated with a selected multiplex line in its operation to select a desired called substation, there are also provided in the incoming connector switch 53 two relays R3225 and R3220. The first of these relays is controlled over a circuit including the extra control wiper 3254 and is provided for the purpose of conditioning the other relay equipment embodied in the switch to repeat received impulses as negative battery pulses over the positive line conductor of a selected called multiplex line. The relay R3220 is arranged to be controlled by the relay R3225 and the busy test relay R3200 and functions to control the ringing operation in signaling over a selected line of the multiplex type. The bank wiring arrangement of the rotary connector switch 3250 is such that the contact set representing the

home position of the switch is utilized in terminating a line accessible to the switch. In order to prevent the idle or busy condition of the line extending to this contact set from interfering with the operation of the switch to select a desired called line, two additional relays R3150 and R3155 are provided in the control apparatus of the switch, which relays are arranged to prevent the premature operation of the line switching relay R3240 during a line selecting operation on the part of the switch.

The apparatus provided at the substations associated with lines of the duplex type terminating at the exchange C is identical in arrangement with the substation apparatus associated with the duplex lines terminating at the exchange B. Thus, the substation equipment provided at the substation T₅ associated with the line 60 is illustrated in Fig. 34 as comprising a transmitter 3459, a receiver 3458, a calling or impulsive device 3493 and a slow-to-release lockout relay R3450 having its winding shunted by an audio frequency by-pass condenser 3454. For the purpose of operatively associating this substation apparatus with the line 60, there is also provided at the substation T₅ a hook switch comprising the receiver supporting arm 3457 and two contact springs 3455 and 3456. There is also provided at this substation a ringer 3460 which is normally connected in series with a condenser 3491 between the line conductor C3481 of the line 60 and ground. In a similar manner, the apparatus provided at the substation T₆ also associated with the line 60 comprises a transmitter 3479, a receiver 3478, a calling device 3494, and a slow-to-release lockout relay R3470 having its winding shunted by an audio frequency by-pass condenser 3474. The signal device provided at this substation is indicated at 3480 and is connected in series with the condenser 3492 between the line conductor C3483 of the line 60 and ground. For the purpose of operatively associating the apparatus provided at the substation T₆ with the line 60, there is also included in this apparatus a hook switch comprising the receiver supporting arm 3471 and the two switch springs 3475 and 3476.

The line circuit associated with the duplex line 60 is substantially similar to that associated with the line 34 and described in the preceding section. More particularly, the line circuit associated with the line 60 and shown in Fig. 34 comprises a differentially wound line relay R3400 which is arranged to operate in response to the initiation of a call at either of the two substations T₅ and T₆, a cut-off relay R3440, a slow-acting lockout relay R3430, and a pair of control relays R3410 and R3420 which are arranged to be controlled by the line relay R3400. The indicated line circuit apparatus also comprises two call registering devices individually corresponding to the substations T₅ and T₆ and having respectively embodied therein operating magnets indicated at 3489 and 3490. The relay R3410 controlled by the line relay R3400 is provided for the purpose of selectively connecting the operating magnets 3489 and 3490 of the call registering devices to be energized in response to the application of ground potential to the extra control conductor C3489 which extends to the bank contacts of the finder switches embodied in the various switching selector repeaters located in the exchange C.

Referring now more particularly to the details of the arrangement of the switching selector re-

peater link 51, this switching unit is illustrated in Figs. 28 and 29 as comprising a finder switch 2800 and a selector switch 2980, each of the well-known rotary type. More particularly, the rotary finder switch 2800 comprises four sets of bank contacts, wipers 2801, 2802, 2803 and 2803' respectively associated with the contact sets, and an operating magnet 2804 for driving the enumerated wipers over the contacts of their respective associated sets. The rotary selector switch 2980 similarly comprises four sets of bank contacts, wipers 2981 to 2984, inclusive, respectively associated with the contact sets and an operating magnet 2985 for driving the enumerated wipers over the contacts of their respective associated contact sets. The link circuit apparatus of the switching selector repeater 51 comprises the usual line and hold relays R2820 and R2825, respectively, and the usual switching relay R2810 which is operative to switch the conductors of a selected calling line through to the line terminals of the line relay R2820 following the operation of the finder switch 2800 to select a calling line. The pulse responsive apparatus embodied in the link circuit comprises a slow-acting relay R2840, a control relay R2850, and a stepping switch 2900 of the well-known minor type. More particularly, this switch is provided for the purpose of determining from the number of impulses making up a first series of impulses transmitted to the link whether or not the call is to be routed over one of the interoffice trunk lines, as, for example, the line 37, to the exchange B, or through one of the local connector switches, as, for example, the switch 54, to another substation line terminating at the exchange C. In brief, the stepping switch 2900 comprises a single set of contacts 2901, a wiper 2902 associated with the contact set 2901, an operating magnet 2903 for driving the wiper 2902 over the contacts of the indicated contact set, a release magnet 2904, and off-normal springs 2905 which are arranged to be closed when the wiper 2902 is stepped away from its home or normal position. These off-normal springs are included in the operating circuit for a control relay R2810 which is operative to prevent more than one series of impulses from being delivered to the operating magnet 2903 and also to prepare the circuit for energizing the release magnet 2904. This relay performs the additional functions of controlling the circuits for impressing dial and busy tone voltages upon the line conductors of the link circuit.

As indicated previously, the arrangement of the switching selector repeater 51 is such that the selector portion thereof operates to select an idle one of the interoffice trunk lines extending to the exchange B and to complete a loop circuit to the repeater associated with the selected trunk line immediately the link is seized. Thereafter and if the character of the first series of impulses transmitted to the link indicates that the call is to be forwarded to another subscriber's line terminating at the exchange C, the seized repeater associated with the selected interoffice trunk line is released and the selector portion of the switch 2980 is caused to again operate to select an idle one of the connector switches provided in the exchange C. For the purpose of controlling the operating magnet 2985 in its operation to perform the two selecting functions just mentioned, there are provided five additional relays R2920, R2930, R2940, R2960 and R2970. More particularly, the three relays R2920, R2930 and R2940 are arranged to operate in response to seizure

5 of the switching selector repeater link and function to initiate the operation of the selector switch 2980 and the partial operation of the line testing relay R2970. The last-mentioned relay, in turn, operates to arrest the operation of the selector switch 2980 when an idle one of the interoffice trunk lines is selected, and also to establish a loop circuit to the repeater, as, for example, the repeater 50 associated with the selected interoffice trunk line. If, thereafter, the character of the first series of impulses transmitted to the link indicates that the call is to be routed to another local subscriber's line terminating at the exchange C, the slow-to-operate relay R2940 is caused to restore to again initiate the operation of the selector switch 2980 and to cause the partial operation of the line testing relay R2960. The last-mentioned relay, in turn, functions to arrest the second operation of the selector switch 2980 when an idle one of the local connector switches is selected, and also to complete a loop circuit to the selected local connector switch. The arrangement of the link circuit apparatus embodied in the switching selector repeater 51 is also so arranged that, if a calling subscriber inadvertently dials a first digit which is not indicative of a local call or a toll call, busy tone is returned to the calling subscriber and the operated switching apparatus succeeding the repeater is released. To this end, there is provided a control relay R2950 which is arranged to operate to cause the functions just mentioned to be performed in the event the wiper 2902 of the minor switch 2900 is not operated to its fourth or its tenth off-normal position, respectively designating local and toll calls, during the first series of impulses transmitted to the switching selector repeater. For the purpose of impressing ground potential upon the extra control wiper 2803', thereby to energize the operating magnet of the call registering device associated with a calling substation when the desired conversational circuit is completed at the called substation, there is provided a back bridge relay R2839 which is of the electropolarized type and is arranged to operate only on local calls and only when a call as routed through the switching selector repeater 51 is answered at a called substation. Finally, the control apparatus embodied in the switching selector repeater 51 includes two thermal relays indicated at 2857 and 2861, respectively, which function to cause the link to be released in the event it is seized by a calling line and no impulses are transmitted thereto within a predetermined time interval following the seizure thereof.

As indicated previously, the switching selector repeater links provided in the exchange C are assigned to the use of calling ones of the lines terminating at this exchange by the distributor 52, which distributor is illustrated in Fig. 30 as comprising a distributor start relay R3050, a pulsing and line testing relay 3040, a secondary testing and distributor hold relay R3030, a plurality of slow-to-release link select relays R3020, R3010, etc., and a control relay R3030 which is operative to initiate the operation of the link select relays corresponding to idle links each time the available idle links have all been assigned for use. More particularly, the start relay R3050 is arranged to operate in response to the application of ground potential to the distributor start conductor C3433 and the relay R3040 is operative in response to operation of the start relay R3050 to cause the operation of the

finder switch of an assigned link to seize the calling line responsible for operation of the start relay. The relay R3040 also functions to arrest the operation of the finder switch embodied in an assigned link when the wipers of the finder switch are operated into engagement with the contacts terminating the conductors of the calling line. The relay R3030 is also arranged to operate when the calling line is found and functions to maintain the start relay R3050 operated until the switching-through operation on the part of the assigned link is fully completed. The relay R3000 functions to complete test circuits over which the link select relays R3010, R3020, etc., are energized when the links respectively corresponding thereto are idle. Each time one of the link select relays is energized over the test circuit extending to its associated link, it is locked in its operated position, thereby to render the associated link available for use. Thereafter and when the respective associated links are respectively assigned to the use of calling lines, the link select relays are caused to restore. Finally, when all of the link select relays occupy their respective restored positions, the control relay R3000 is conditioned to be energized to recomplete the test circuits for the respective link select relays.

Referring now more particularly to the details of the local connector switch 54, this switch is illustrated in Fig. 33 as comprising a rotary stepping switch 3390 having bank contacts at which the conductors of the subscribers' lines extending to the exchange C terminate. More particularly, the rotary switch 3390 comprises five sets of bank contacts, wipers 3391 to 3395, inclusive, respectively associated with the bank contact sets, and an operating magnet 3396 for driving the wipers over the contacts of their respective associated sets. The control apparatus embodied in the local connector switch 54 comprises the usual line and hold relays indicated at R3310 and R3315, respectively, and also a slave relay R3320 which is arranged to be controlled by the slow-acting hold relay R3315 and performs the switching functions normally assigned to the hold relay. The control apparatus of the indicated switch further includes a busy test relay R3350, a slow-to-operate line switching relay R3380 which is operative to initiate the ringing operation in signaling over a selected called line, a slow-acting ring cut-off relay R3365, and a slave relay R3370 under the control of the ring cut-off relay R3365 which performs the line switching operations normally assigned to the ring cut-off relay. For the purpose of controlling the operating and holding circuits for the busy test and line switching relays R3350 and R3380, respectively, and for additional control purposes described in detail hereinafter, there are provided three additional relays R3330, R3333 and R3340, the first and last of which are both arranged to operate at the beginning of each series of impulses transmitted to the incoming connector switch and to remain operated for the duration of each impulse series. The relay R3333 is provided for controlling the operation of the rotary switch operating magnet 3396 during the release of the local connector switch. The control apparatus of the switch further includes a back bridge or battery reversing relay R3300 which is operative to reverse battery over the conductors of the trunk lines incoming to the switch when a call routed by way of the switch is answered at a selected called

75 substation. As indicated previously, the lines terminating in the bank contacts of the local connector switch 54 are of three different types, namely, single party lines, lines of the duplex type, and lines of the multiplex type having individually associated therewith station selecting apparatus arranged to respond to negative battery pulses transmitted thereto over the positive sides of the associated lines. In order to 10 condition the control apparatus of the local connector switch 54 to transmit negative battery pulses over the positive side of a selected multiplex line in response to a final series of impulses transmitted thereto from a calling telephone station, the extra control wiper 3393 and the bank contact set associated therewith are embodied in the rotary switch 3390, and a relay R3360 arranged to be controlled over a circuit including the wiper 3393 is embodied in the 15 switch control apparatus. The bank wiring arrangement of the switch 3390 is such that the contact set representing the home position of the switch is utilized in terminating a line accessible to the switch. In order to prevent the 20 idle or busy condition of the line terminating at this contact set from interfering with the operation of the switch to select a desired called line, there is provided an additional relay R3346, which relay is arranged to prevent the premature operation of the line switching relay R3380 during a line selecting operation on the part of the switch.

SECTION 5.—THE APPARATUS PROVIDED IN THE EXCHANGE E

35 The automatic switching equipment provided in the exchange E is substantially similar in construction and arrangement to the apparatus provided in the exchange C. Thus, the switching selector repeater 80, the distributor 81 and the local connector switch 82 are identical with the corresponding switching units 51, 52 and 54 provided in the exchange C and described in the preceding section of the specification. The incoming connector switches provided in the exchange E are, however, slightly different from the corresponding switching units located in the exchange C. More particularly, the incoming connector switch 84 located in the exchange E is illustrated in Figs. 24 and 25 as comprising a rotary line selecting switch 2550 having bank contacts at which the subscribers' lines extending to the exchange E are terminated. These bank contacts are divided into five levels having wipers 2551 to 2555, inclusive, respectively associated therewith. The switch 2550 also includes an operating magnet 2561 which is operative to drive the enumerated wipers over the contacts of their respective associated contact sets. The control apparatus embodied in the incoming connector switch 84 includes a relay R2400 which is operative selectively to connect the conductors of the trunk line 31' to the conductors of the trunk line 83 extending to the bank contacts of the switching selector repeater 80 or to the conductors of the link line incoming to the switch 84. On calls outgoing from the exchange E to the exchange B, the relay R2400 is energized from ground as applied to the control conductor C2409 of the trunk line 83 when the last-mentioned line is seized whereas, on calls incoming to the exchange E from the exchange B and routed over the trunk line 31', the indicated relay remains in its restored position. The control apparatus embodied in the incoming con-

necter switch 84 further includes the usual line and hold relays R2420 and R2425, respectively, and a slave relay R2430 which is controlled by the slow-acting hold relay R2425. In addition, there are provided a slow-to-release busy test relay R2460, a slow-to-operate line switching relay R2530 which is operative to initiate the ringing operation in signaling over a selected called line, a slow-acting ring cut-off relay R2540 and a slave relay R2520 which is under the control of the cut-off relay R2540 and performs the line switching operations normally assigned to the ring cut-off relay. For the purpose of controlling the operating and holding circuits for the busy test relay R2460 and the operating circuit for the line switching relay R2530, and for additional control purposes described in detail hereinafter, there are provided two relays R2440 and R2450 which are arranged to operate at the beginning of each series of impulses transmitted to the incoming connector switch 84 and remain operated until after each impulse train is ended. After connections routed by way of the incoming connector switch 84 are completed, supervision thereof is maintained through the provision of a battery reversing relay R2410 which is arranged to be energized in series with a line balancing impedance element 2498 when a call routed through the incoming connector switch to a desired called substation is answered. For the purpose of controlling the operation of the rotary switch operating magnet 2561 during the release of the incoming connector switch 84, there is provided therein a relay R2435, the energization of which is partially determined by the position of the switch wiper 2554 in the manner explained more in detail hereinafter.

As indicated previously, the lines extending to the exchange E and terminating in the bank contacts of the connector switch 84 are, like the lines extending to the exchanges B, C and D, of three different types, namely, single party lines, lines of the duplex type and lines of the multiplex type. The lines of the last-mentioned character individually have associated therewith station selecting apparatus which is operative to connect the substation apparatus provided at a called substation to the associated line in response to a particular series of negative battery impulses transmitted thereto over the positive side of the associated line. For the purpose of causing a final series of impulses transmitted to the incoming connector switch to be repeated as negative battery pulses over a selected line of the multiplex type, the extra control wiper 2553 and the contact set associated therewith are embodied in the rotary switch 2550 and two additional relays R2500 and R2510 are included in the link circuit apparatus of the switch. These relays are operative to prevent a third series of impulses transmitted to the switch from effecting further operation of the rotary switch 2550 and also to cause corresponding pulses of negative battery potential to be transmitted over the positive side of the selected line. These two relays, in cooperation with the busy test relay R2460, also function to cause ringing current to be projected over a selected called line of the multiplex type and, in cooperation with the ring cut-off relay R2540 and the slave relay R2520 controlled thereby, are operative to cause the ringing operation to be arrested and the desired conversational circuit to be established when the call is answered at the selected called substation.

The bank wiring arrangement of the lines terminating at the contacts of the rotary switch 2550 is such that the twenty-fifth set of contacts is utilized to terminate one of the subscribers' lines extending to the exchange B. This twenty-fifth set of contacts represents the normal or home position of the wipers embodied in the switch 2550 and, thus, it will be apparent that the wipers are normally standing in engagement with a set of contacts terminating one of the subscribers' lines. In order to prevent the premature operation of the switching relay R2530 when the incoming connector switch 84 is seized over the trunk line 31', there is provided a relay R2405 which functions to hold the operating circuit for the line switching relay R2530 open until after the wipers of the switch 2550 have been moved from engagement with their respective associated twenty-fifth contacts in response to the dialing operation performed at the calling telephone station.

The arrangement of the control apparatus embodied in the incoming connector switch 84 is such that it responds to an unbalanced condition of an established loop circuit extending thereto by operating to set up a toll offering connection to a selected called line even though the line is busy. More particularly, there is provided a differentially wound relay R2415 which is arranged to respond to an unbalanced loop circuit condition of the character mentioned and, in cooperation with a second relay R2470 and the busy test relay R2460, functions to cause the desired toll offering connection to be established to the selected busy line. These three relays, in cooperation with certain of the other relay equipment embodied in the connector switch circuit, also function to cause ringing current to be projected over the selected called line when the previously established connection involving this line is released, and to cause the desired conversational circuit to be completed between the calling and called telephone stations when the call is thereafter answered at the called substation.

45 SECTION 6.—ESTABLISHING A LOCAL CONNECTION BETWEEN TWO SUBSCRIBERS' LINES TERMINATING AT EXCHANGE B.

In establishing connections between the subscribers' lines extending to the exchange B, only the local finder-connector links provided in this exchange are utilized. For example, if a party at the substation T₃, illustrated in Fig. 22, initiates a call intended for the substation T₂ and illustrated in Fig. 21, by removing his receiver from its supporting hook, a direct current bridge is placed across the line conductors C1381 and C1383, in the usual manner, at the calling substation. When this bridging path is completed, the line relay R2250 is energized over a circuit which may be traced as extending from ground at RA2264 by way of C1383, the above mentioned bridging path, C1381, RA2265 and the winding of R2250 to battery. Upon operating, the relay R2250 completes, at RA2253, a path for applying battery potential to the control conductor C1382', thereby to mark the calling line in the bank contacts of each of the finder switches having access to this line. This path extends from the negative terminal of the exchange battery through the winding of R2260 and by way of RA2257 and RA2253 to C1382'. At RA2252, the relay R2250 completes an obvious path for applying ground potential to the control conductor C1382, thereby to mark the calling line as busy 75 in the bank contacts of the connector switches

at which the calling line is terminated. At RA2251, the relay R2250 completes an obvious path for applying ground to the distributor start conductor C2328, thereby to energize the start relay R2230 of the link distributor in series with the rotary switch operating magnet 2205. More particularly, the relay R2230 is energized over a circuit extending from ground at RA2251 by way of RA2256, C2328, RA2227, the winding of R2230, RA2226, the magnet armature 2206 and the winding of the magnet 2205 to battery. Due to the relatively high resistance of the winding of R2230, the magnet 2205 is not sufficiently energized to operate when the above-traced circuit is completed. The relay R2230, however, operates to complete, at RA2235, an obvious multiple holding circuit for the all-links-busy relay R2225, which latter relay is maintained energized so long as any of the local finder-connector links provided in the exchange B are idle. At RA2234, the relay R2230 completes an obvious circuit for energizing the pendulum type relay R2220, causing the latter relay to attract its operating armature RA2221 and thus initiate vibratory movement of the weighted armature 2222 in the usual manner. The two armatures RA2221 and 2222 of the relay R2220 are included in an obvious circuit for energizing the upper winding of R2215, which latter relay includes a lower winding normally short-circuited at RA2217 and, hence, is slow to operate. Due to the vibratory operation of the armature 2222, the circuit for energizing the upper winding of R2215 is only intermittently completed and this relay does not immediately operate. When the vibratory movement of the armature 2222 is substantially arrested this armature settles into resting engagement with RA2221, the operating circuit including the upper winding of R2215 is closed and this relay operates.

During the interval following the operation of the relay R2220 and before the relay R2215 operates, the finder portion of the link corresponding to the position occupied by the wipers of the distributor switch 2200 is caused to operate to seize the calling line. For purposes of this description, it will be assumed that the wipers of the distributor switch noted are standing in engagement with the contacts corresponding to the finder-connector link illustrated in Figs. 19 and 20 when the relay R2230 operates. With the wipers of the distributor switch 2200 in this position, the relay R2230 upon operating in the manner just described, opens, at RA2232 and its associated resting contact, a point in the circuit, traced hereinafter, for energizing the operating magnet 2205 by way of the circuit interrupting magnet armature 2206. At RA2231, the relay R2230 completes a path for applying ground to the hold conductor C2275 individual to the finder-connector link illustrated. When ground is applied to the last-mentioned conductor, the line relay R2035 embodied in the link illustrated in Figs. 19 and 20 is energized over a circuit which may be fully traced as extending from ground at RA2231 by way of the wiper 2202, the resistor 2282, C2275, RA2041 and the upper winding of R2035 to battery. At RA2233, the relay R2230 completes an obvious circuit for energizing the slow-acting relay R2240, which latter relay, upon operating, completes at RA2241 a multiple circuit for energizing the upper winding of R2035, which multiple circuit substantially parallels the operating circuit for R2035 traced above. At RA2243, the relay R2240, upon operating, prepares a test

5 circuit, traced hereinafter, for energizing the upper winding of R2245 when the finder switch 2070 embodied in the selected finder-connector link is operated to the position corresponding to the calling line.

Before describing the operation of the finder switch 2070 to search for the calling line, it is pointed out that, when the above-traced operating circuit for the line relay R2035 is completed, 10 this relay operates to complete, at RA2036, an obvious circuit for energizing the slow-acting hold relay R2010. The last-mentioned relay, upon operating, completes, at RA2012, a circuit for energizing the upper winding of the slow-acting relay R2005, this circuit extending from ground at the off-normal spring 2016 by way of the spring 2016, RA2012 and the upper winding of R2005 to battery. At RA2011, the relay R2010, upon operating, applies ground potential to the conductor C1989, thereby to prepare holding circuits for various ones of the relays mentioned hereinafter, and to complete a circuit for energizing the heating coil 2063 of the bimetallic relay 2062, this circuit extending by way of the grounded conductor C1989, RA1913, C1982, the heating element 2063 and the resistor 2065 to battery. When ground is applied to C1989 the slow-to-release relay R2030 is energized over a circuit extending by way of this grounded conductor, RA1953, 20 C1990 and the winding of R2030 to battery. When energized over this circuit the relay R2030 operates to prepare, at RA2031 and RA2032, a path traced hereinafter for impressing booster battery potential upon the control conductor of the calling line. At RA2014, the hold relay R2010 applies ground potential to C1992, thereby to prepare holding circuits for additional ones of the relays illustrated in Figs. 19 and 20. At RA2015, the relay R2010 opens a point in the circuit, traced 25 hereinafter, utilized to energize the release magnet 2033 embodied in the Strowger switching mechanism 1900 of the connector portion of the link. The slow-to-release relay R2005, upon operating, prepares at RA2007 an impulsive circuit, traced hereinafter, for energizing the vertical magnet 2008 of the Strowger switching mechanism 1900 in accordance with the impulses making up the first digit dialed at the calling substation. At RA2006, the relay R2005 completes an 30 obvious circuit for energizing the relay R2000, which latter relay, upon operating, completes at RA2002 a path for applying ground potential to the ringing and tone apparatus start conductor C2008', thereby to initiate in the usual manner the operation of the ringing and tone apparatus provided in the exchange B. The last-mentioned path may be traced as extending from ground by way of RA2021, C1988, RA1952, C1988 and RA2002 to the start conductor C2008'. At RA2004 and RA2004', the relay R2000 prepares a path, traced hereinafter, for applying dial tone voltage to the loop extending to the calling subscriber's substation. At RA2001, the relay R2000 completes an 35 obvious multiple circuit for energizing the heating coil 2063 of the bimetallic thermal relay 2062. Following the operation of R2000 in the manner just described, the relay apparatus embodied in the finder-connector link is conditioned to respond to the first series of impulses dialed at the calling substation.

As indicated previously, when the relay R2230 operates, it completes a circuit for energizing the operating magnet of the finder switch 2070, thereby to initiate the operation of this switch to search for the calling line. More particularly, the

operating magnet 2056 of the switch 2070 is energized over a circuit extending from ground at RA2233 by way of RA2246, the wiper 2204, C2278, and the winding of the magnet 2056 to battery. When energized over this circuit, the magnet 2056 steps the wipers 2071 to 2073 of the switch 2070 one step and completes, at its armature 2057, a circuit extending by way of C2280 for energizing the lower winding of R2245. When the lower winding of R2245 is energized, this relay operates to open at RA2246 a point in the above-traced operating circuit for the magnet 2056. The resulting deenergization of the magnet 2056 conditions this magnet to step the enumerated wipers of the finder switch 2070 a second step. Also, when the magnet 2056 is deenergized, the circuit for energizing the lower winding of R2245 is interrupted at the armature 2057, causing the relay R2245 to restore to re-complete at RA2246 the operating circuit for the operating magnet 2056. Thus, the magnet 2056 and the relay R2245 interact and the periodic energization of the magnet causes the wipers of the finder switch 2070 to be driven over the contacts of their respective associated contact sets until they are moved into engagement with the contacts terminating the conductors of the calling line 33. More particularly, when the wiper 2072 is moved into engagement with the contact terminating the control conductor C1382' of the line 33, the above-mentioned test circuit including the upper winding of R2245 is completed, this circuit extending from ground at RA2243 by way of the upper winding of R2245, the wiper 2203, C2726, the lower winding of R2050, the wiper 2072, C1382', C2276, RA2253, RA2257 and the winding of the cut-off relay R2260 to battery. When its upper winding is energized over the above-traced circuit, the relay R2245 is held operated independently of the energized or deenergized condition of its lower winding and in its operated position maintains the above-traced operating circuit for the magnet 2056 open at RA2246. Thus the operation of the finder switch 2070 is arrested.

When its lower winding is energized over the above-traced test circuit, the relay R2050 operates to complete at the "X" contact associated with RA2052 a circuit for energizing its upper winding, which circuit extends from ground at RA2011 by way of the contacts 2059 of the thermal relay 2058, RA2023, RA2052 and the upper winding of R2050 to battery. Following the completion of the circuit just traced, the relay R2050 completes its operation to open at RA2055 and its associated resting contact one multiple path for maintaining ground on C2277 and to complete at RA2055 and its associated working contact a circuit extending by way of C2274, the wiper 2201 and RA2242 for energizing the distributor switch operating magnet 2205. At RA2051 and RA2054, the relay R2050 extends the calling loop circuit through to the line terminals of the line relay R2035. More particularly, with the relay R2050 operated, the line relay R2035 is energized over a circuit which may be traced as extending from ground by way of the secondary winding of the coupling transformer 2009, RA2004, RA2004', the lower winding of R2035, RA2046, RA2054, the wiper 2073, C1383, the bridge across C1383 and C1381 at the calling substation, C1381, the wiper 2071, RA2051, RA2041 and the upper winding of R2035 to battery. Since an alternating dial tone voltage is induced in the secondary winding of the

transformer 2009, it will be understood that the usual dial tone signal is produced by the receiver at the calling substation when the circuit just traced is completed. At RA2053, the relay R2050 completes a path for applying ground potential to the conductor C1382' of the calling line 33, this path extending from ground at RA2011 by way of the contacts 2059, RA2023, RA2052, RA2053 and the wiper 2072 to the conductor C1382'. When ground potential is applied to the conductor C1382', the cut-off relay R2260 is energized over a circuit extending by way of C1382', RA2253, RA2257 and the winding of R2260 to battery. The relay R2260 now operates to complete at RA2262 an obvious holding circuit for itself and to prepare, at RA2263, a circuit, traced hereinafter, for energizing the operating magnet 2270 of the call register device associated with the calling line. At RA2261, the relay R2260 completes an obvious circuit for energizing the slow-acting lockout relay R2255, which latter relay operates after an interval to open at RA2256 a point in the path, traced previously, for applying ground potential to the start conductor C2328. At RA2257, the lockout relay R2255 opens a point in the path traced previously, for impressing marking battery potential upon the control conductor C1382'. At RA2264 and RA2265, the cut-off relay R2260 opens two points in the above-traced operating circuit for the line relay R2250, causing the last-mentioned relay to restore and open at RA2252 a point in the path, mentioned above, for applying ground potential to the control conductor C1382. Immediately R2250 restores, an alternative path is completed for making the calling line as busy in the bank contacts of the connector switches to which this line extends, this path extending by way of the grounded control conductor C1382', RA2262 and RA2252 to the conductor C1382. At RA2251, the relay R2250, upon restoring, opens a further point in the path for applying ground potential to the start conductor C2328.

When ground is disconnected from the start conductor the start relay R2230 restores and opens, at RA2234, a point in the operating circuit for R2220, causing the latter relay to restore to open, at RA2221, a point in the operating circuit for R2215. If the finder switch 2070 operates to seize the calling line without undue delay the weighted armature 2222 is still vibrating and the relay R2215 is in its restored position at the time the relay R2220 falls back. At RA2233, the relay R2230, upon restoring, opens the operating circuit for R2240 and a further point in the above-traced operating circuit for the finder switch operating magnet 2056. At RA2235, the relay R2230 opens the multiple holding circuit for R2225. At RA2231, the relay R2230 opens a point in the original operating circuit for the line relay R2035 embodied in the operated finder-connector link. When the relay R2240 restores, it opens at RA2243 a point in the above-traced test circuit by way of which the lower winding of R2050 and the upper winding of R2245 were energized in series, causing the last-mentioned relay to restore. At RA2241 the relay R2240 opens a point in the above-traced multiple circuit for energizing the upper winding of R2035.

Immediately the relay R2050 fully operates, the rotary switch 2200 embodied in the distributor is started in operation to position its wipers on the contacts corresponding to the next available idle link. More particularly, when R2050 op-

erates, it completes at RA2055 the above-traced circuit for energizing the magnet 2205. Upon operating, the magnet 2205 opens at its associated armature 2206 a point in the previously traced operating circuit for the start relay R2230, thus insuring the restoration of this relay even though a second call is awaiting the assignment of a finder-connector link such that ground potential is retained on the start conductor C2328 after the line relay R2250 restores in the manner previously explained. When the relay R2240 restores shortly following the restoration of R2230 it opens, at RA2242, a point in the above-traced circuit for energizing the operating magnet 2205 of the distributor switch 2200. The resulting deenergization of this magnet permits the ratchet and pawl mechanism associated therewith to advance the wipers 2201 to 2204, inclusive, one step or into engagement with the contacts corresponding to the next finder-connector link. If this next link is idle, the guard conductor extending thereto is open-circuited so that no further circuit is available for energizing the magnet 2205. On the other hand, if the link next succeeding that illustrated is busy, ground potential is present on the guard conductor extending thereto, whereby an alternative circuit is completed for energizing the magnet 2205, this alternative circuit extending by way of the grounded wiper 2201, RA2232, RA2226, the armature 2206 and the winding of the magnet 2205 to battery. It will be noted that the completion of this circuit results in the short-circuiting of the winding of R2230, providing ground potential is present on the start conductor C2328. This short-circuiting path extends by way of the grounded wiper 2201 by way of RA2232, the winding of R2230, RA2227 and RA2256 to the grounded armature RA2251. The completion of this path prevents the start relay R2230 from reoperating during the hunting operation of the distributor switch 2200 even though a second call is awaiting the assignment of a finder-connector link. When the magnet 2205 is energized over the above-traced alternative circuit, it again attracts its associated armature to interrupt the circuit and thus cause its own deenergization. When the magnet 2205 is deenergized the second time, the ratchet and pawl mechanism associated therewith advances the wipers of the switch 2200 a second step. This stepping operation on the part of the distributor switch 2200 is continued until the wipers of the switch are positioned on the contacts corresponding to the next available idle link. Thus, when the wiper 2201 is driven into engagement with a contact terminating a guard conductor extending to an idle link, the absence of ground potential upon the guard conductor of the selected link prevents the magnet 2205 from again being energized and, hence, the stepping operation of the switch 2200 is arrested. Also the absence of ground on the guard conductor corresponding to the selected idle link permits the start relay R2230 to be energized in series with the magnet 2205 provided a second call is awaiting the assignment of an idle link. If no call is waiting at the time the wipers of the switch 2200 are present on the contact corresponding to the next available link, the start relay remains deenergized until the next succeeding call is initiated. In this regard, it is pointed out that the operation of the cut-off relay R2260, followed by the restoration of the line relay R2250, occurs substantially simultaneously with the comple-

tion of the original operating circuit for the magnet 2205 and, hence, the line relay R2250 is caused to restore to remove ground from the start conductor C2328 before the hunting operation of the distributor switch 2200 is completed. Thus, the possibility of two links being assigned to the same calling line is obviated.

As pointed out previously, the relay R2225 is provided for the purpose of preventing the distributor switch 2200 from continuously operating to search for an idle link when all of the finder-connector links are busy. Referring now in greater detail to this feature of the circuit, it is pointed out that the conductor C2271 is multipled to the corresponding contact springs of the relays corresponding to and including R2050 and individually embodied in the respective links. When any one of the links is idle, the relay embodied therein which corresponds to R2050 is in its restored position so that ground potential is maintained on C2271. On the other hand, when all of the links are busy, all of these relays are operated and ground potential is removed from the conductor noted. Upon the removal of ground from C2271, the relay R2225 is deenergized and restores to open at RA2226 a point in the above-traced alternative circuit for energizing the operating magnet 2205 of the distributor switch 2200. Hence, shortly following the operation of the last available link to seize a calling line and the resulting restoration of R2230 and R2240 in the manner explained above, the operation of the distributor switch is arrested until one of the links becomes idle to terminate the all-links-busy condition. At RA2227, the relay R2225, upon restoring, opens a point in the above-traced operating circuit for the start relay R2230, thereby to prevent the operation of this relay in response to a call initiated at a time when all of the links are busy. At RA2228, the relay R2225 opens a point in its own holding circuit as traced above. Obviously, when the all-links-busy condition is terminated through the release of one of the operated links, the relay embodied in the released link and corresponding to R2050 of the link illustrated, restores to again apply ground to C2271, whereby the all-links-busy relay R2225 is again energized and reoperates. Upon operating, this relay completes at RA2226 the previously traced alternative circuit for energizing the operating magnet 2205 of the distributor switch 2200, thereby to initiate the operation of this switch to position its wipers on the contacts corresponding to the idle link. At RA2227, the relay R2225 reprepares the above-traced operating circuit for the start relay R2230. Finally, the relay R2225 reprepares, at RA2228, its own holding circuit.

As indicated above, the two relays R2215 and R2220 are provided for the purpose of causing a second link to be assigned to the use of a calling line in the event the finder portion of a first assigned link fails to find the calling line within a predetermined time interval. Thus, in the case considered above, if the finder switch 2070 fails to find the calling line 33 to cause the restoration of the distributor start relay R2230 within the time interval required for the vibratory movement of the armature 2222 to cease and the relay R2215 to operate, the operation of this finder switch is arrested and a second finder-connector link is assigned to the use of the calling line. More particularly, when the armature 2222 settles into resting engagement with RA2221, the relay R2215 operates, after an interval, to open, at RA2217, a point in the path short-circuiting its lower wind-

ing, and to complete, at RA2216, an obvious circuit for energizing the magnet 2205. When this magnet is energized, it attracts its associated armature 2206 to open a point in the above-traced operating circuit for the start relay R2230, causing the last-mentioned relay to restore. Upon restoring, the relay R2230 opens, at RA2234, the operating circuit for R2220 and, at RA2233, the operating circuit for R2240. The relay R2230, upon restoring, also opens a point in the above-traced operating circuit for the magnet 2056 embodied in the finder switch 2070, whereby the operation of this switch is arrested. With the two relays R2230 and R2240 restored the above-traced operating circuit for the line relay R2035 is interrupted and this relay restores to cause the restoration of the operated relays R2010, R2005, R2000 and R2030 and the deenergization of the thermal relay R2062. Thus, the first assigned link, namely the link shown in Figs. 19 and 20, is entirely released. When the relay R2220 restores, it opens, at RA2221 and the armature 2222, the operating circuit for R2215, causing the latter relay to restore to open, at RA2216, the alternative operating circuit for the magnet 2205. When the magnet 2205 is deenergized, the ratchet and pawl mechanism therewith associated operates to advance the wipers 2201 to 2204, inclusive, of the distributor switch 2200 one step or into engagement with the contacts corresponds to the next succeeding link. If this next link is busy, ground potential is present on the guard conductor thereof so that the winding of R2230 is short-circuited and an alternative circuit is completed for energizing the magnet 2205, this alternative circuit being traced above and extending by way of the armature 2206. When energized over this alternative circuit, the magnet 2205 operates to open the alternative circuit, whereby the magnet 2205 is again deenergized to permit the associated ratchet and pawl mechanism to advance the wipers of the switch 2200 a second step. Due to the circuit-interrupting action of the armature 2206, the wipers are driven over the contacts of their respective associated sets until they are positioned on the contacts corresponding to the next available idle link. When the wipers reach this position, the absence of ground potential on the guard conductor extending to the idle link prevents the magnet 2205 from again being energized and the operation of the distributor switch 2200 is arrested. Also, when the wiper 2201 engages the contact terminating the guard conductor extending to the idle link, the short-circuiting path for the winding of R2230 is interrupted and this relay is again energized in series with the winding of the magnet 2205. Upon operating, the relay R2230 initiates the operation of the finder portion of the selected idle link to search for the calling line in the manner set forth above. Obviously, if the second link assigned to the calling line also fails to find the line the cycle of operations just described is repeated.

As pointed out above, when the switching relay R2050 operates, dial tone current is projected over the calling line to the calling substation T₃ and the resulting operation of the receiver provided at this substation indicates to the calling subscriber that the dialing operation may be started. The line relay R2035 follows the impulses making up the digits dialed at the calling substation and functions to repeat the impulses of the first digit to the vertical magnet 2008 of the Strowger switch 1900. More particularly, during the open circuit period of each impulse

of the first digit, the relay R2035 restores to complete a circuit for energizing the vertical magnet 2008 in parallel with the lower winding of R2005, this circuit extending from ground at RA2036, by way of RA2013 to RA2007, where it divides, one branch extending through the winding of the magnet 2008 to battery and the other branch extending through the lower winding of R2005 to battery. Also, during the open circuit period of each impulse, the operating circuit for the hold relay R2010 is interrupted, but due to the slow-to-release characteristic of this relay, it remains operated during impulsion. The repeated energization of the vertical magnet 2008 causes this magnet in cooperation with its associated ratchet and pawl mechanism to elevate the wipers of the Strowger switching mechanism 1900 step by step in a vertical direction to a position opposite the level of bank contacts corresponding to the number of impulses making up the first digit. Thus, if the first digit comprises three impulses, the wipers 1901 to 1904, inclusive, are elevated three steps in a vertical direction or to a position opposite the third level of bank contacts. When these wipers are moved the first step in a vertical direction, the off-normal springs 2034 are closed to prepare a circuit, traced hereinafter, for energizing the release magnet 2033; the off-normal springs 2017 are closed to complete a multiple path shunting the armature RA2002 for maintaining ground potential on the ringing and tone apparatus start conductor C2008' independently of the relay R2000; and the off-normal springs 2016 and 2016' are disengaged to open a point in the previously traced circuit for energizing the upper winding of R2005. During the first series of impulses, the lower winding of R2005 is repeatedly energized over the impulsion circuit and, due to the slow-to-release characteristic of this relay, it remains operated until the first series of impulses is terminated. During the first vertical step taken by the wipers 1901 to 1904, inclusive, an obvious path is completed, at the off-normal springs 2016 and 2017', for applying multiple ground to the guard conductor C2274, thereby to maintain the finder-connector link of Figs. 19 and 20 marked as busy in the bank contacts of the distributor switch 2200.

At the end of the first series of impulses and during the inter-digit pause between the first and second digits, the line relay R2035 is held energized for a time interval sufficient to permit the slow-acting relay R2005 to restore. Upon restoring, the relay R2005 opens, at RA2006, the operating circuit for R2000, which latter relay restores in turn to open, at RA2002, the multiple path for applying ground potential to the ringing and tone apparatus start conductor C2008'. At RA2004 and RA2004', the relay R2000, upon restoring, opens a point in the path, traced above, for impressing dial tone voltage upon the calling loop circuit. At RA2004' and RC2003', the relay R2000 substitutes ground at RC2003' for ground at the upper terminal of the secondary winding of the transformer 2009 in the loop circuit extending to the calling substation T₃ and including the winding of the line relay R2035. At RA2001, the relay R2000 opens the multiple circuit for energizing the heating coil 2063 of the bi-metallic thermal relay 2062.

When the relay R2005 restores, it opens, at RA2007 and its associated working contact, a point in the above traced circuit by way of which the winding of the vertical magnet 2008 and the lower winding of R2005 were energized in paral-

lel during the impulses of the first digit. At RA2007 and its associated resting contact, the relay R2005 prepares a circuit for energizing the rotary magnet 1974 of the Strowger switching mechanism 1900 in series with the slow-acting relay R1930 during the impulses of the second digit.

As pointed out in the general description of the apparatus illustrated in Figs. 19 and 20, the lines terminating in the bank contacts of the Strowger switching mechanism 1900 are of four different types, namely, single party lines, duplex lines, multiplex lines, and trunk lines requiring a switching-through operation on the part of the connector portion of the link. The arrangement is such that the control apparatus embodied in the connector switch of each link operates in a different manner depending upon the character of the line to be selected, the different types of operation being required for the reason that: when a single party or duplex line is to be selected, it is not necessary that impulses be transmitted over the selected line after the two line selecting digits are dialed at the calling substation whereas, if a called subscriber's line of the multiplex type is to be selected, an additional series of impulses must be transmitted over the line to the station selecting apparatus associated with the line for the purpose of operatively connecting the substation apparatus at the called substation to the called line. Also, if the line to be selected is a trunk line leading to an impulse repeater or to the trunk line terminating apparatus provided at the operator's position in the exchange B, it is necessary that a switching-through operation be performed by the connector portion of the operated link in order that further impulses dialed at the calling sub-station may be transmitted to the seized repeater or the supervisory lamp provided at the operator's position may be controlled. To accommodate the different types of operation on the part of the connector switches, the lines extending thereto are grouped in a particular manner and the operation of the switches is made partially dependent upon the level of bank contacts selected by the vertical movement of the switch wipers. More particularly, the multiplex lines are terminated in the lowermost levels of the bank contact field of the switching mechanism 1900 and the contact fields of the other similar Strowger switching mechanisms. For example, if twenty-five multiplex lines are terminated at the bank contacts of the switch 1900, the first two levels and half of the third level are utilized in terminating the conductors of these lines. The last half of the third level and the succeeding levels may be used to terminate single party or duplex subscribers' lines. The switching mechanism further comprises an extra control bank contact field having contacts arranged to be encountered by the extra control wiper 1903. In the assumed arrangement, wherein the third level terminates both multiplex and single party or duplex lines, the multiplex lines are terminated at the first five sets of contacts in the level and the duplex or single party lines are terminated at the last five sets of contacts in the level. The sixth extra control contact of this third level, namely, that corresponding to the first single party or duplex line, is connected to ground through a resistance of approximately one thousand ohms so that, when the wiper 1903 encounters this contact during rotary movement thereof, the relay R1960 is caused to operate for a purpose explained hereinafter. The arrange-

ment is such that, when the wipers are elevated to the first level of contacts following the last contact level terminating lines of the multiplex type, the off-normal springs 1997 are caused to operate to complete an alternative circuit for energizing the relay R1960. Also, the arrangement is such that when the wipers of the Strowger switching mechanism 1900 are operated to a position opposite a level of bank contacts terminating lines requiring a switching-through operation on the part of the connector switch, the off-normal spring 2091 is operated from its normal position, as shown in the drawing, to its off-normal position, thereby to engage the spring 2093 and to complete a circuit for partially energizing the switching-through relay R2040, all in the manner explained in detail hereinafter.

Continuing now with the operation of the finder-connector link, when the second digit is dialed at the calling substation, the line relay R2035 again follows the impulses and repeats the same to the rotary magnet 1974 of the Strowger switching mechanism 1900. More specifically, during the open circuit period of the first impulse of the second digit, the line relay R2035 restores to complete a circuit for energizing the rotary magnet 1974, the slow-acting relay R1930 and the lower winding of the slow-acting relay R1920, this circuit extending from ground at RA2036 by way of RA2013, RA2007, RA2044, C1991, RA1946 and the winding of R1930, where it divides, one branch extending by way of RA1918 and the winding of the magnet 1974 to battery, and the other branch extending by way of RA1932 and the lower winding of R1920 to battery. At the end of the open circuit period of each impulse the circuit, just traced, is interrupted. Each time the magnet 1974 is energized it advances the wipers of the switching mechanism 1900 one step in a rotary direction. The relay R1930 operates when the above-traced circuit is first completed and, due to its slow-to-release characteristic, remains operated throughout the series of impulses. Upon operating, the relay R1930 completes, at RA1932 and its associated working contact, an obvious holding circuit for the relay R1920. At RA1931, the relay R1930 opens a point in the circuit, traced hereinafter, for energizing the busy test relay R1940, thereby to prevent the busy test relay from operating during rotary movement of the wipers embodied in the Strowger switching mechanism 1900 and when the test wiper 1902 engages test contacts terminating the control conductors of busy subscribers' lines. The slow-acting relay R1920, upon operating, completes, at RA1922, an obvious circuit for energizing the slave relay R1925. At RA1921, the relay R1920 opens a point in the circuit, traced hereinafter, for energizing the slow-to-operate line switching relay R1910. When the relay R1925 operates RA1926, it prepares or completes, depending upon the character of the called lines, a circuit, traced hereinafter, for energizing the switching-through relay R2040. At RA1929, the relay R1925 opens a point in the path, traced hereinafter, for conducting busy tone current by way of the calling loop circuit to the calling substation in the event the called line is ultimately found busy. At RA1928', the relay R1925 prepares a circuit, described hereinafter, for energizing the relays R1935 and R1960. At RA1927 and RA1928, the relay R1925 prepares the circuit, mentioned above and traced hereinafter, for energizing the busy test relay R1940 in the event the selected called line is found busy.

As pointed out above, during the impulses of the second digit, the rotary magnet 1974 is energized in accordance with the impulses making up the digit so that, at the conclusion of the digit, the wipers 1901 to 1904, inclusive, are positioned on the contacts terminating the conductors of the called line. For example, if the called line 34 is the sixth line in the third level of bank contacts, which level terminates five lines of the multiplex type and five lines of the duplex or single party type, the second digit dialed at the calling substation will necessarily comprise six impulses so that, at the conclusion thereof, the wipers 1901, 1902 and 1904 are respectively positioned on the contacts terminating the conductors C1384, C1385 and C1386. Also, with the wipers in this position, the extra control wiper 1903 engages the contact 1998 corresponding to the selected called line. With the wiper 1903 in this position, a circuit is completed for energizing the relay R1960 in parallel with the relay R1935, this circuit extending from ground by way of the resistor 1999, the contact 1998, the wiper 1903, and RA1915 to RA1928', where it divides, one branch extending by way of RA1963 and the winding of R1960 to battery, and the other branch extending by way of the armature 1975 and the winding of R1935 to battery. Due to the resistance of the resistor 1999 and the relatively high resistance of R1935, the last-mentioned relay does not operate when energized over the circuit just traced. The relay R1960, however, partially operates, when energized over this circuit, to complete, at the "X" contacts associated with RA1962, a holding circuit for itself, which circuit extends from ground at RA2014 by way of C1992, RA1982 and the winding of R1960 to battery. Following the completion of this circuit, to complete, at the "X" contacts as open, at RA1963, a point in its operating circuit as traced above and to prepare, at RA1961 and RA1965, a circuit, traced hereinafter, for energizing the slow-acting ring cut-off relay R1970. At RA1964, the relay R1960 opens a point in a path, traced hereinafter, for short-circuiting the upper winding of R1920.

Shortly following the end of the second series of impulses dialed at the calling substation, the relay R1930 restores to interrupt, at RA1932, the holding circuit for the relay R1920 and to complete the above-traced test circuit for determining the idle or busy condition of the called line 34. As indicated previously, if the called line 34 is busy, ground potential is present upon the control conductor thereof. On the other hand, if the called line is idle, battery potential is impressed upon the control conductor C1385 thereof through the winding of the cut-off relay R2120. Assuming that the called line is busy at the time it is selected, when the relay R1930 restores, the busy test relay R1940 is energized over the above-mentioned test circuit which may be traced as extending by way of the grounded conductor C1385, the wiper 1902, RA1927, RA1928, RA1931 and the winding of R1940 to battery. The relay R1940 now operates to prepare a holding circuit for itself, which circuit is completed in response to the sequential restoration of the two relays R1920 and R1925 shortly following the restoration of the relay R1930. The holding circuit for the busy test relay R1940 may be traced as extending from ground at RA2011 by way of C1989, RA1944, RA1928, RA1931 and the winding of R1940 to battery. At RA1942, the relay R1940, upon operating,

opens a point in the circuit, traced hereinafter, for energizing the upper winding of the line switching relay R1910. At RA1943, the relay R1940 prepares a multiple circuit, traced hereinafter, for energizing the switching-through relay R2040. At RA1945, the relay R1940 completes an obvious path for short-circuiting the upper winding of R1920, thereby to render the last-mentioned relay slow-to-release. At RA1946, the relay R1940 opens a point in the impulsing circuit, traced above, by way of which the slow-acting relay R1930 was energized in series with the rotary magnet 1974. At RA1948, the relay R1940 completes a circuit for projecting busy-tone current over the calling line to energize the receiver at the calling substation. More particularly, the path of this current may be traced as extending from the ungrounded terminal of the busy tone current source, not shown, by way of RA1919', the condenser 1973, RA1929, RA1948, C1996, the condenser 2019, RA2046, RA2054, the wiper 2073, C1383, the receiver at the calling substation, C1381, the wiper 2071, RA2051, RA2041, the upper winding of R2035 and the exchange battery to the grounded terminal of the ringing current source. The resulting operation of the receiver provided at the calling substation indicates to the calling subscriber that the desired conversational connection cannot immediately be established. Following receipt of the busy tone signal, the calling subscriber is expected to hang up to initiate the release of the operated switch train. The manner in which the operated fender-connector link is restored to normal when the connection is cleared out at the calling substation is described in detail hereinafter.

If the called line 34 is idle at the time it is selected by the switching mechanism 1900, battery potential is present on the control conductor C1385 thereof so that, when the relay R1930 restores, the busy test relay R1940 is short-circuited and does not operate. Shortly thereafter, and when R1925 restores, a circuit is completed for energizing the upper winding of the line switching relay R1910, this circuit extending from ground at RA2011 by way of the off-normal springs 2091 and 2092, C1983, RA1942, the upper winding of R1910, RA1921, RA1927, the wiper 1902, C1385, RA2142 and the winding of the cut-off relay R2120 to battery. When its upper winding is energized over this circuit, the relay R1910 partially operates, after an interval, to complete, at the "X" contacts associated with RA1917, a circuit for energizing its lower winding, this circuit extending from ground at RA2014 by way of C1992, RA1917 and the lower winding of R1910 to battery. Following the completion of the circuit just traced, the relay R1910 completes, at RA1914, an obvious path for applying ground potential directly to the control conductor C1385, thereby to mark the called line 34 as busy in the bank contacts of the connector switches having access to the called line. At RA1915, the relay R1910 opens a point in the above-traced operating circuit for the relay R1960. At RA1918, the relay R1910 prepares an alternative circuit, traced hereinafter, for energizing the relay R1930 during operation of the connector switch to transmit impulses to the station selecting apparatus associated with a selected called line of the multiplex type. At RA1919', the relay R1910 opens a point in the previously traced circuit for projecting busy tone current over the calling line to the receiver at the calling substation. At RA1911 and RA1918, the relay R1910 prepares a circuit,

traced hereinafter, for energizing the ring cut-off relay R1970 when the call is answered at the called substation T₂. At RA1913, the relay R1910 interrupts the circuit, traced previously, for energizing the heating coil 2063 of the thermal relay 2062, thereby to arrest the operation of this relay. When the armature RA1911 is operated into engagement with its associated working contact, ringing current is projected over the line 34 to energize the signal device provided at the called substation T₂. More particularly, the path of the ringing current may be traced as extending from the ungrounded terminal of the ringing current source by way of the exchange battery, the winding of the slow-acting ring cut-off relay R1970, RA1961, RA1951, RA1911, the wiper 1901, C1384, RA2111, the pulsing springs of the calling device 2184, the hook switch springs 2171 and 2170, the signal device 2182 and the condenser 2183 to the grounded terminal of the ringing current source. At RA1911 and RA1912, a circuit is also completed in response to the operation of R1910 for projecting a portion of the ringing current by way of the calling loop circuit to energize the receiver provided at the calling substation. This circuit may be traced as extending from the ungrounded terminal of the ringing current source by way of the exchange battery, the winding of R1970, RA1961, RA1951, RA1911, RA1912, the condenser 1912', C1980, the condenser 2018, RA2041, RA2051, the wiper 2071, the line conductor C1381, the receiver at the calling substation C1383, the wiper 2073, RA2054, RA2048, the lower winding of R2035 and RA2004' to the grounded terminal of the ringing current source at C2003'. The resulting operation of the receiver provided at the calling substation indicates that the desired substation is being rung, and the operation of the signal device 2182 provided at the called substation serves to signal 40 the called party.

It will be noted that, with the arrangement illustrated, ringing current is only projected over one side of the called line, thus providing selective energization of the signal device located at the desired called substation. In order that the other substation associated with the called line 34, namely, the substation T₁, may be signaled to the exclusion of the substation T₂, the line 34 is terminated at two different sets of contacts in the bank contact field of each of the connector switches to which it extends, the two line conductors C1384 and C1386 being reversely connected to the line contacts in the respective two contact sets. Thus, when a calling party dials the directory number designating a desired one of the two substations T₁ and T₂, the resulting operation of the connector switch determines the side of the line over which the ringing current will be projected. For example, had the substation T₁ been called instead of the substation T₂, the wipers of the switching mechanism 1900 would have been operated into engagement with the other set of contacts, not shown, but also terminating the conductors of the line 34. In this case, the wiper 1901 would have been left standing in engagement with the contact terminating the line conductor C1386 of the called line 34 at the conclusion of the rotary movement of the switch wipers and, hence, operation of the line switching relay R1910 would have resulted in the projection of ringing current over the line conductor C1386 to energize the signal device 2180 provided at the substation T₁ rather than over the line conductor C1384 utilized in ener- 75

gizing the signal device 2182 provided at the substation T₂. By virtue of this arrangement, selective signaling of the two substations associated with a duplex line is obtained.

As explained above, when ground potential is applied to the control conductor C1385 of the called line 34 in response to the operation of the line switching relay R1910, the cut-off relay R2120 is energized over the circuit extending by way of the grounded control conductor C1385, RA2142 and the winding of R2120 to battery. When energized over this circuit, the relay R2120 operates to complete at RA2126 an obvious circuit for energizing the slow-acting lockout relay R2130, which latter relay, upon operating, prepares at RA2132 and its associated working contact, a holding circuit for itself and opens, at RA2132 and its associated resting contact, a point in the path for applying ground potential to the distributor start conductor C2328. At RA2131, the relay R2130 opens a point in the circuit, traced hereinafter, for energizing the cut-off relay R2120 on calls routed by way of the line 34 and initiated at the substations T₁ and T₂. At RA2121 and RA2126, the relay R2120, upon operating, disconnects the line terminals of the relay R2160 from the line conductors C1384 and C1386, thereby to clear the called line of impedances which might interfere with the transmission of voice frequency currents. At RA2123 and RA2124, the relay R2120 completes a path for applying ground potential to the control conductor C2178 associated with the line 34 and extending to the finder switches of the respective links at which the line 34 is terminated. The path for applying ground potential to C2178 extends from the grounded conductor C1385 by way of RA2142 and RA2124 to the conductor C2178.

When the call is answered at the substation T₂, the hook switch provided at this substation is operated to its off-normal position to open the springs 2171 and 2170 and to close the springs 2171 and 2172. At the springs 2170 and 2171, the above-traced circuit for energizing the signal device 2182 is interrupted. At the springs 2171 and 2172, a circuit is completed for energizing the lockout relay R2100, provided at the substation T₁, in series with the ring cut-off relay R1970, this circuit extending from ground at RC2103 by way of RA2102, the winding of R2100, the transmitter 2173, the receiver 2174, the switch springs 2172 and 2171, the pulsing springs of the calling device 2184, RA2111, C1384, the wiper 1901, RA1911, RA1951, RA1961, and the winding of R1970 to battery. When energized over this circuit, the lockout relay R2100 operates to complete a series holding circuit including the respective windings of R1970 and R2100, which circuit may be traced as extending from ground at RA1965 by way of RA1955, RA1919, the wiper 1904, C1386, RA2101, RA2102, the winding of R2100, the transmitter 2173, the receiver 2174, the switch springs 2172 and 2171, the pulsing springs of the calling device 2184, RA2111, C1384, the wiper 1901, RA1911, RA1951, RA1961 and the winding of R1970 to battery. At RA2101 and its associated resting contact, the relay R2100 effectively disconnects the apparatus provided at the substation T₁ from the line conductor C1386, thereby to lock this substation out of service during the interval when the line 34 is occupied with the call to the substation T₂. Thus, the connection is guarded against intrusion through the initiation of a call at the substation T₁ until the connection to the substation T₂ is released. The ring cut-off relay R1970

is of the slow-to-operate type, such that it does not operate in response to the energization furnished by the ringing current traversing its winding during the ringing operation. When, however, the above-traced circuit is completed for energizing the winding of this relay in series with the winding of R2100 provided at the substation T₁, it operates to complete at RA1971 a circuit for energizing the relay R1950, which circuit extends from ground at RA2014 by way of C1992, RA1971 and the winding of R1950 to battery. When energized over the circuit just traced, the relay R1950 first completes, at the "X" contacts associated with RA1954, a holding circuit for itself, which circuit also extends from ground at RA2014 and by way of C1992, RA1954 and the winding of R1950 to battery. At RA1953, the relay R1950, upon fully operating, opens a point in the previously traced operating circuit for R2030. At RA1952 and its associated resting contact, the relay R1950 interrupts the path by way of which ground potential is applied to the ringing and tone apparatus start conductor C2008'. At RA1952 and its associated working contact, the relay R1950 completes an alternative circuit for energizing the heating coil 2063 of the thermal relay 2062, this circuit extending from ground by way of RA2021, C1986, RA1952, C1982, the heating coil 2063 and the resistor 2085 to battery. At RA1951 and RA1955, the relay R1950 completes the desired talking circuit between the calling and called substations and in so doing, opens two points in the circuit by way of which ringing current is projected over the called line to energize the signal device at the called substation and two points in the circuit by way of which the windings of R1970 and R2100 are being held energized in series. At RA1951, a point is also opened in the circuit, traced previously, by way of which ring-back tone current is projected over the calling loop circuit to energize the receiver at the calling substation. The ring cut-off relay R1970 restores shortly following the operation of R1950 to interrupt, at RA1971, the operating circuit for the last-mentioned relay.

Immediately the relay R1950 operates a circuit is completed for energizing the two windings of the back bridge relay R2020 in series with the winding of the slow-to-release lockout relay R2100 provided at the substation T₁. This circuit may be traced as extending from ground at the upper terminal of the lower winding of R2020 by way of this lower winding, C1996, RA1955, RA1919, the wiper 1904, C1386, RA2101, RA2102, the winding of R2100, the transmitter 2173, the receiver 2174, the hook switch springs 2172 and 2171, the pulsing springs of the calling device 2184, RA2111, C1384, the wiper 1901, RA1911, RA1951, C1980 and the upper winding of R2020 to battery. Upon operating, the relay R2020 completes, at RA2022 and RA2023, the previously mentioned path for applying booster battery voltage to the control conductor C1382' of the calling line 33, thereby to cause the operation of the message register device associated with the calling line. More particularly, the circuit for energizing the operating magnet 2270 of the register device extends from the left terminal of the booster battery voltage source 2131' by way of RA2031, RA2032, RA2022, RA2023, RA2052, RA2053, the wiper 2072, C1382', RA2263 and the winding of the magnet 2270 to ground. When energized over this circuit, the magnet 2270 attracts its associated armature 2271 so that the ratchet wheel 2272 is advanced one step to cause 75

the device to register the call. Shortly following the operation of R2020 to complete the above-traced circuit for energizing the operating magnet 2270 of the call register device, the slow-to-release relay R2030, which is deenergized in response to the operation of R1950, restores to open, at RA2031 and RA2032, a point in the operating circuit for the magnet 2270. At RA2032 and its associated resting contact, the relay R2030 applies ground to the control conductor C1382' over a path similar to that just traced, thereby to maintain the relays R2050, R2260 and R2255 operated and to maintain the calling line 33 marked as busy in the bank contacts of the connector switches having access to this line.

At RA2021 and its associated resting contact, the back bridge relay R2020, upon operating, opens a point in the above-traced alternative circuit for energizing the heating element 2063 of the thermal relay 2062, thereby to arrest the operation of this thermal relay. At RA2021 and its associated working contact, the relay R2020 applies multiple ground to the release conductor C1989. Following the operation of the back bridge relay R2020, the desired conversational circuit is fully established and no further operation of the switching apparatus occurs until the connection is released at both the calling and called substations. It will be noted that with the desired talking circuit fully established talking battery voltage is impressed upon the loop extending to the called substation through the windings of the back bridge relay R2020 whereas talking battery voltage is impressed upon the loop extending to the calling substation through the windings of the line relay R2035. It will further be noted that the winding of the lockout relay R2100 provided at the substation T₁ is included in the talking circuit. In order to prevent the impedance of this winding from interfering with the transmission of voice frequency currents over the established connection the audio frequency by-pass condenser 2104 is connected in shunt with the winding of R2100. For the same reason, the condenser 2114 is provided at the substation T₂ in shunt with the winding of the lockout relay R2110.

From the foregoing description, it will be apparent that the purpose of providing the two lockout relays R2100 and R2110 is that of guarding an established connection extending to one of the substations against intrusion occasioned by the initiation of a call at the other substation associated with the line before the established connection is released. Thus, in those cases where the substation T₁ is the calling or called substation rather than the substation T₂, the lockout relay R2110 functions to disconnect the apparatus provided at the substation T₂ from the line conductor C1384. The manner in which the slow-to-release lockout relay R2110 is energized on calls incoming to the substation T₁ is substantially identical with the mode of operation of the relay R2100 provided at the substation T₂, and will readily be apparent from the preceding description.

The release of the connection is primarily under the control of the calling party. Thus, if the called party at the substation T₂ hangs up before the connection is cleared out at the calling substation, the above-traced circuit by way of which the windings of R2100 and R2020 are being held energized in series is interrupted at the springs 2171 and 2172 of the hook switch provided at the called substation T₂. Upon restoring, the relay

R2100 operatively associates the apparatus provided at the substation T₁ with the line 34 so that calls may be initiated and received at this substation. The back bridge relay R2020, upon restoring, removes, at RA2021 and its associated working contact, multiple ground from the conductor C1988. At RA2021 and its associated resting contact, the relay R2020 recompletes the above-traced alternative circuit for energizing the heating element 2063 of the thermal relay 2062. At RA2022 and RA2023, the relay R2020, upon restoring, opens a point in the alternative holding circuits for R2050 and R2260 and recompletes the previously traced original holding circuits for these relays.

When the connection is cleared out at the calling substation, the calling loop circuit is interrupted causing the line relay R2035 to restore and open, at RA2036, the operating circuit for the hold relay R2010. When the hold relay restores, it opens, at RA2011, the respective holding circuits for the relays R1940, R2050 and R2068 and also a point in the above-traced alternative circuit for energizing the heating element 2063 of the thermal relay 2062. At RA2014, the relay R2010, upon restoring, opens a point in the respective holding circuits for the relays R1910, R1950 and R1960, causing all of these relays to restore. When the relay R1910 restores, it removes, at RA1914, ground potential from the control conductor C1385 of the called line 34, thereby to remove the busy marking from this line and to open the operating circuit for the cut-off relay R2120. The cut-off relay R2120 now restores, to open at RA2125 the operating circuit for the lockout relay R2130, causing the latter relay to restore. Thus, the line circuit apparatus associated with the called line 34 is restored to normal and the called line is marked as idle in the bank contacts of the connector switches to which this line extends, negative battery potential being impressed upon the control conductor C1385 to identify the line 34 as idle through the winding of the cut-off relay R2120. In a similar manner, when ground potential is removed from the conductor C1988 to open the holding circuits for R2050 and R2260, these two relays restore and battery potential is impressed upon the control conductor C1382 of the calling line through the winding of the cut-off relay R2260. When the relay R2260 restores, it opens at RA2261 the operating circuit for the lockout relay R2255, causing the last-mentioned relay to restore. Thus, the line circuit apparatus associated with the calling line 33 is restored to normal.

When the hold relay R2010 restores in the manner pointed out above, it opens, at RA2013, a point in the above-traced operating circuit for the two relays R1930 and R1920 and completes at R2015 the previously mentioned circuit for energizing the release magnet 2033, this latter circuit extending from ground at the lower terminal of the winding of the release relay R2210 by way of this winding, C2282, RA2015, RA2045, the off-normal springs 2034 and the winding of the magnet 2033 to battery. When energized over this circuit, the relay R2210 operates to complete, at its two armatures RA2211 and RA2212, circuits, not shown, for energizing signal or metering devices associated with the local finder-connector links provided in the exchange B. When the release magnet 2033 is energized, it attracts its associated armature, not shown, and causes the wipers of the Strowger switching mechanism 1900 to be returned to rotary and 75

vertical normal in the usual manner at which time the off-normal springs 1997, 2016, 2017, 2081 and 2034 are returned to their respective normal positions. When returned to normal, the springs 2034 are disengaged to open the operating circuit for the magnet 2033 and, when the spring 2016 is moved from engagement with its associated contact spring 2017 and into engagement with the spring 2016, ground potential is removed from the guard conductor C2274, thereby to identify the finder-connector link illustrated in Figs. 19 and 20 as idle in the bank contacts of the distributor switch 2200. Following the release of the switching mechanism 1900 in the manner just described, the established connection is fully released.

The manner in which a local call is routed from a substation associated with a subscriber's line of the duplex type by way of the finder-connector link illustrated in Figs. 19 and 20 to another local line extending to the exchange B is substantially similar to the mode of establishing the connection between the substations T₃ and T₂, as described above. The manner in which the line circuit associated with a line of the duplex type operates, is, however, considerably different from the mode of operation of the line circuits individually associated with the single party lines. Thus, if a party at the substation T₂ initiates a call intended for the substation T₃ and the link illustrated in Figs. 19 and 20 is utilized in setting up the connection, the operation of the apparatus is initiated when the calling party removes the receiver 2174 from its supporting hook to cause the hook switch provided at the substation T₂ to be operated to the off-normal position. In response to this operation, the switch springs 2170 and 2171 are opened to disconnect the signal device 2182 from the line conductor C1384 and the springs 2171 and 2172 are closed to complete a circuit for energizing the lower winding of R2160 in series with the winding of the lockout relay R2100, this circuit extending from ground at RC2103 by way of RA2102, the winding of R2100, the transmitter 2173, the receiver 2174, the springs 2172 and 2171, the pulsing springs of the calling device 2184, RA2111, RA2126 and the lower winding of R2160 to battery. Due to the relatively high resistance of the lower winding of R2160, the relay R2100 does not operate when energized over the circuit just traced. The relay R2160, however, operates to complete, at RA2163, an obvious circuit for energizing the two relays R2140 and R2150 in parallel. At RA2162, the relay R2160 prepares a circuit for energizing its upper winding. At RA2161 and RA2164, the relay R2160 reverses the connections of the line conductors C1386 and C1384 to the link line conductors C2177 and C2179 extending to the bank contacts of the finder switch 2070. At RA2151, the relay R2150, upon operating, prepares a circuit, traced hereinafter, for energizing the operating magnet 2176 embodied in the metering device associated with the substation T₁. The relay R2140, upon operating RA2142, applies ground potential to the control conductor C1385 of the line 34, thereby to mark this line as busy in the bank contacts of the connector switches to which it extends. At RA2141, the relay R2140 completes a path for marking the calling line 34 in the bank contacts of the finder switches to which the line 34 extends, this path extending from the negative terminal of the exchange battery by way of the winding of R2120, RA2131,

RA2141 and C2178 to the control bank contacts of the various finder switches having access to the line 34. At RA2143, the relay R2140 completes a path extending by way of RA2132 for applying ground potential to the distributor start conductor C2328, whereby the operation of the distributor illustrated in Fig. 22 and of the finder switch 2070 illustrated in Fig. 20 is initiated. The manner in which the distributor switch and the finder switch 2070 cooperate to cause the last-mentioned switch to find the calling line is exactly the same as described previously with reference to the call initiated at the substation T₃. Immediately the wipers of the finder switch 2070 are moved into engagement with the contacts terminating the conductors C2171 to C2179, inclusive, ground potential is impressed upon the control conductor C2178 over a path extending from ground at RA2243 by way of the upper winding of R2245, the wiper 2203, C2276, the lower winding of R2050 and the wiper 2072 to C2178. When ground potential is applied to C2178 in the finder-connector link circuit, the cut-off relay R2120 is energized over a circuit extending by way of RA2141, RA2131 and the winding of R2120 to battery. When energized over this circuit, the relay R2120 first closes the "X" contacts respectively associated with RA2122 and RA2124. At the last-mentioned contacts, the relay R2120 completes an obvious holding circuit for itself and thereafter completes its operation. Shortly following the operation of R2120, the switching relay R2050 is energized and operates to impress negative battery potential through the upper winding of the line relay R2035 upon the negative line conductor C2179. At RA2122, the cut-off relay R2120, upon operating, completes a circuit extending from ground at RA2162 for energizing the upper winding of R2160. The last-mentioned relay is of the differential type, such that when both of its windings are energized, it restores. Upon restoring, the relay R2160 opens, at RA2162, a point in the circuit for energizing its upper winding. Substantially simultaneously with the restoration of R2160, the relay R2120 completes its operation to disconnect, at RA2121 and RA2126, the line terminals of the two windings of R2160 from the line conductors C1384 and C1386. Thus, the relay R2160 remains in its restored position for the duration of the call. At RA2125, the relay R2120, upon fully operating, completes an obvious circuit for energizing the slow-acting lockout relay R2130, which latter relay, upon operating, opens, at RA2132, a point in the path for applying ground to the distributor start conductor C2328 and opens, at RA2131, a point in the operating circuit for the cut-off relay R2120. When the relay R2160 restores, it opens, at RA2163, the operating circuit for the two relays R2140 and R2150 causing both of these relays to restore. When the relay R2150 falls back, it opens, at RA2151 and its associated working contact, a point in the circuit for energizing the operating magnet 2176 of the metering device associated with the substation T₁. At RA2151 and its associated resting contact, the relay R2150 connects the winding of the operating magnet 2175, embodied in the metering device associated with the substation T₂, to the control conductor C2178, whereby the magnet 2175 may be energized in response to the application of booster battery potential to C2178 when the desired connection is ultimately established. The relay R2140, upon restoring, opens, 75

at RA2143, a point in the holding circuit for the lockout relay R2130 and, at RA2141, a further point in the operating circuit, traced previously, for R2120. At RA2142, the relay R2140 connects the control conductor C1385 to the control conductor C2178 so that busying ground potential is applied to the first-mentioned control conductor through the finder switch of the operated link.

10 When negative battery potential is impressed upon the line conductor C2179 through the upper winding of the line relay R2035 embodied in the operated link, the energization furnished the lockout relay R2100 is sufficient to cause the operation of this relay. Specifically, this relay is now energized over a circuit extending from battery as applied to C2179 by way of RA2164, RA2111, the pulsing springs of the calling device 2184, the springs 2171 and 2172, the receiver 2174, the transmitter 2173, the winding of R2100 and RA2102 to ground at RC2103. Upon operating, the lockout relay disconnects the apparatus provided at the substation T₁ from the line conductor C1386 to guard the line 34 against intrusion through the initiation of a call at the substation T₁ during the time interval when this line is occupied with the call initiated at the substation T₂. Also, upon operating, the relay R2100 completes, at RA2101 and RA2102, the calling loop circuit by way of which the two windings of the line relay R2035 are energized in series with the winding of R2100, which loop circuit is believed to be obvious from the preceding description.

35 During the dialing operation performed at the calling substation, the loop circuit, mentioned above, is interrupted at the pulsing springs embodied in the calling device 2184 a number of times determined by the digits of the directory 40 number identifying the called substation. The manner in which the connector portion of the link illustrated in Figs. 19 and 20 responds to the impulses to select the called line and the manner in which the called line is tested to determine 45 the idle or busy condition thereof are in all respects identical with the operation of the apparatus as described above with reference to the call initiated at the substation T₃. If the called line is found to be idle, ringing current is projected thereover, ring-back tone is returned to the calling substation, and ground potential is impressed upon the control conductor C1382 of the called line to guard the line against intrusion on other calls incoming thereto. When ground 50 potential is impressed upon C1382, the cut-off relay R2260 is energized over a circuit extending by way of this conductor, RA2252 and the winding of R2260 to battery. Upon operating, the relay R2260 completes, at RA2261, the operating 55 circuit for the slow-acting lockout relay R2255, which latter relay, upon operating, opens a point in the path, traced previously, for applying ground potential to the distributor start conductor C2328. The cut-off relay R2260, upon 60 operating, also disconnects, at RA2265, the winding of the line relay R2250 from the line conductor C1381. At RA2264, the cut-off relay R2260 removes ground potential from the line conductor C1383. Thus, the called line is cleared 65 of all impedances which might interfere with the transmission of voice frequency currents. When the call is answered at the called substation, the back bridge relay R2020 embodied in the operated link is caused to operate, in the manner explained previously, and, upon operating, ap- 70

plies booster battery potential to the control conductor C2178 of the line 34, thereby to energize the operating magnet 2175 embodied in the metering device individually associated with the calling substation T₂ and to cause the metering device to register the call. Following the operation of the back bridge relay, the desired conversational connection is fully completed.

The manner in which the connection, as established between the two substations T₂ and T₃, is released is substantially similar to the release of the apparatus as explained previously. Thus, when the calling subscriber at the substation T₂ hangs up, the loop circuit by way of which the relays R2100 and R2035 are being held energized in series, is interrupted at the springs 2171 and 2172, causing both of these relays to restore. When the line relay R2035 restores, it opens the operating circuit of the hold relay R2010, which latter relay, upon restoring, initiates the release of the operated link in the manner explained above. When the link is released, ground is removed from each of the two control conductors C2178 and C1382, respectively embodied in the lines 34 and 33. The relay R2100, upon restoring, functions, in the manner explained previously, operatively to associate the apparatus provided at the substation T₁ with the line 34. When ground potential is removed from the control conductor C2178, the cut-off relay R2120 and the lockout relay R2130 are caused to restore in the order named and in an obvious manner, thus restoring the line circuit associated with the line 34 to normal. Similarly, when ground potential is removed from the control conductor C1382, the cut-off and lock-out relays R2260 and R2255, respectively are caused to return the line circuit apparatus associated with the line 33 to normal.

If the call intended for the substation T₃ is initiated at the substation T₁ rather than the substation T₂, the switching relay R2160 is energized and remains operated for the duration of the call. More particularly, when the receiver 2168 is removed from its supporting hook to initiate the call, the hook switch provided at the substation T₁ is moved to its off-normal position to open the springs 2165 and 2166 and to close the springs 2166 and 2167. At the last-mentioned pair of springs, a circuit is completed for energizing the upper winding of R2160 in series with the winding of the lockout relay R2110, this circuit extending from ground at RC2113 by way of RA2112, the winding of R2110, the transmitter 2169, the receiver 2168, the springs 2167 and 2166, the pulsing springs embodied in the calling device 2185, RA2101, RA2121 and the upper winding of R2160 to battery. Due to the relatively high resistance of the upper winding of the relay R2160, the lockout relay R2110 does not operate when energized over the circuit just traced. The relay R2160, however, operates to perform the functions described above, namely, to complete, at RA2163, the operating circuit for the two relays R2140 and R2150 and to reverse the connections of the line conductors C1384 and C1386 to the link line conductors C2177 and C2179. In this case, when the finder portion of the seized link operates to seize the line 34 and ground is returned over the control conductor C2178 from the operated link to cause the operation of the cut-off relay R2120, the latter relay completes, at RA2122, a multiple holding circuit for the upper winding of R2160, the lower winding of the latter relay remaining deenergized. Thus, the re-

lay R2160 is not caused to restore. Also, when the calling line 34 is seized by the finder portion of the operated link, battery potential is impressed upon the line conductor C2179 in the manner explained previously, causing the lockout relay R2110 to be energized over a circuit extending by way of C2179, RA2161, RA2101, the pulsing springs embodied in the calling device 2185, the switch springs 2166 and 2167, the receiver 2168, the transmitter 2169, the winding of R2110 and RA2112 to ground at RC2113. The current traversing this circuit is of sufficient magnitude to cause the operation of the lockout relay R2110, which relay, upon operating, disconnects the apparatus provided at the substation T₂ from the line conductor C1384, thereby to guard the connection against intrusion through the initiation of a call at the substation T₂. It will be noted that, with the relay R2160 operated, the relay 2150 is also in its operated position so that the operating circuit for the operating magnet embodied in the metering device associated with the substation T₁ is prepared at the operated armature RA2151. Hence, when the call is answered at the called substation, to cause booster battery potential to be impressed upon the control conductor C2178, the operating magnet 2176 is energized over a circuit extending by way of the conductor C2178, RA2123, RA2151 and its associated working contact, and the winding of the magnet 2176. The resulting operation of the magnet 2176 causes the metering device individually associated with the substation T₁ to register the call. Thus, it will be apparent that, by virtue of the particular line circuit arrangement, the two metering devices having respectively embodied therein the magnets 2175 and 2176 are caused selectively to operate depending upon which of the two substations T₁ and T₂ is the calling substation in an established connection routed by way of the line 34. During the release of the connection established as a result of the call initiated at the substation T₁, the line circuit associated with the line 34 is returned to normal in response to the removal of ground potential from the control conductor C2178. More particularly, when ground potential is removed from C2178, the cut-off relay R2120 restores to cause the sequential restoration of the two relays R2160 and R2130. When the relay R2160 restores, it opens, at RA2163, the operating circuit for the two parallel connected relays R2140 and R2150, causing both of these relays to restore. Thus, the line circuit associated with the line 34 is returned to normal.

As explained previously, if a call initiated at one of the subscriber's substations and routed to the finder-connector link illustrated in Figs. 19 and 20 is to be extended to a substation associated with a line of the multiplex type, it is necessary that a third series of impulses be transmitted through the finder-connector link to the station selecting apparatus associated with the called multiplex line in order operatively to associate the substation apparatus provided at the desired substation with the called line. To this end, the control apparatus of the link is so arranged that the relay R1960 is not caused to operate when a line of the multiplex type is selected. More particularly, the off-normal springs 1997 operate only after the wipers of the Strowger switching mechanism 1900 have been elevated to a position above the last level of bank contacts terminating lines of the multiplex type.

If the last level of contacts at which lines of this type are terminated also contains contact sets terminating lines of the single party or duplex type, the bank wiring of this level is arranged in the manner explained previously; that is, the multiplex lines are terminated at the contacts first engaged by the wipers of the mechanism 1900 during the rotary movement thereof and the single party and duplex lines are terminated in the succeeding contact sets of the level, the resistor 1999 being connected to provide a circuit for energizing the relay R1950 when the wipers of the switching mechanism 1900 are rotated to the position corresponding to the first single party or duplex line in the level. Thus, the relay R1960 does not operate when a line of the multiplex type is selected. If it be assumed now that the call initiated at the substation T₂, for example, is to be routed to a substation on a line of the multiplex type, the response of the connector portion of the link illustrated in Figs. 19 and 20 is such that the wipers 1901 to 1904 inclusive are positioned on the contacts terminating the desired line when the two line selecting digits are dialed. At the end of the second digit, if the called line tests idle, the relay R1910 is caused to operate and locks itself in its operated position in the manner explained previously. Following the operation of this relay, the control apparatus embodied in the connector portion of the link is conditioned to repeat the impulses of the third series to the station selecting apparatus associated with the called line. Also, with the relay R1910 operated and the relay R1960 restored a path is completed for impressing negative battery potential upon the positive side of the selected line, this path extending from the negative terminal of the exchange battery by way of the resistor 1976, C1993, RA2037, C1994, RA1965, RA1955, RA1919 and the wiper 1904 to the positive line conductor of the called line. When the relay R1910 operates to impress ground potential upon the control conductor of the called line, the station selecting apparatus associated with the selected line is seized and conditioned to respond to impulses transmitted thereto. In the arrangement illustrated, the impulses are repeated as battery potential pulses which are transmitted over the path just traced to the operated station selecting apparatus associated with the called line. Thus, at the beginning of the first impulse of the third digit, the relay R2035 restores to open, at RA2037, a point in the above-traced path extending from battery to the positive line conductor of the called line. At the end of each open circuit pulse, this path is obviously recompleted at RA2037. Upon restoring at the beginning of the first impulse of the third series, the relay R2035 also completes, at RA2036, an alternative circuit for energizing the relays R1930 and R1920, this circuit extending from ground at RA2036 by way of RA2013, RA2007, RA2044, C1991, RA1946 and the winding of R1930, where it divides, one branch extending by way of RA1918 and the resistor 1972 to battery, and the other branch extending by way of RA1932 and the lower winding of R1920 to battery. Upon operating, the relay R1930 completes, at RA1932, an obvious holding circuit for R1920 and opens, at RA1931, a point in the previously traced circuit for energizing the busy test relay R1940. The relay R1920, upon operating, completes, at RA1922, the circuit for energizing the relay R1925 and opens, at RA1921, a point in the circuit, traced previously, for ener-

gizing the upper winding of R1910. When the relay R1925 operates, it opens, at RA1921 and its associated resting contact, a further point in the operating circuit for R1910 and prepares, at RA1927 and its associated working contact, a circuit, traced hereinafter, for energizing R1940. At RA1928, the relay R1925 prepares the circuit, traced previously, for energizing the relay R1960. At the end of the third series of impulses dialed at the calling substation, the line relay R2035 remains operated to hold the above-traced operating circuit for the relay R1930 interrupted at RA2036. The relay R1930 now restores to open, at RA1932, the holding circuit for R1920 and to complete, at RA1931, the circuit for energizing R1940, which latter circuit may be traced as extending from ground at RA1914 by way of RA1927, RA1928, RA1931 and the winding of R1940 to battery. Upon operating, the relay R1940 prepares, at RA1944, its holding circuit as traced previously, which holding circuit is completed in response to the sequential restoration of R1920 and R1925 in the manner explained above. At RA1942, the relay R1940 opens a further point in the operating circuit for R1910 and, at RA1943, it prepares a point in the circuit, traced hereinafter, for energizing the relay R2040. At RA1945, the relay R1940 short-circuits the upper winding of R1920. At RA1946, the relay R1940 opens a point in the above-traced circuit for energizing the two relays R1920 and R1930. At RA1947, the relay R1940 short-circuits the impulsive springs associated with RA2037 of the line relay R2035. At RA1948, the relay R1940 prepares a point in the circuit, traced previously, for projecting busy tone over the loop circuit extending to the calling substation, this circuit now being held open at the operated armature RA1919 of the switching relay R1910. At RA1941, the relay R1940 completes the patch, traced previously, by way of which ringing current is projected over the called line to energize the signal device provided at the called substation and ring-backtone current is projected over the calling line to signal the calling subscriber that the called substation is being rung. When the call is answered at the called substation, ground potential is impressed upon the negative line conductor of the called line to energize the relay R1970, which relay upon operating, completes the circuit, traced previously, for energizing the switching relay R1950. The relay R1950, upon operating, completes the desired connection between the calling and called substations and extends the called loop circuit to the windings of the back bridge relay R2020. The resulting operation of the back bridge relay causes booster battery potential momentarily to be applied to the control conductor associated with the calling line for the purpose of energizing the metering device associated with the calling substation in the manner previously explained. It is pointed out that if the selected multiplex line tests idle, the busy test relay R1940 operates in the manner explained previously and, upon operating, shunts, at RA1947, the pulsing springs of the line relay R2035, thereby to prevent negative battery pulses corresponding to the impulses of the final digit from being impressed upon the positive side of the selected line.

The manner in which a connection routed to a substation of the multiplex type is released is in all respects similar to the release of the connection as described above with reference to the call initiated at the substation T₃. More par-

ticularly, the release of the connection is under the control of the calling party and is initiated when the connection is cleared out at the calling substation to cause the sequential restoration of the line and hold relays R2030 and R2010, respectively. The last-mentioned relay, upon restoring, opens the holding circuits for the operated relays R1910, R1940 and R1950 and closes the circuit for energizing the release magnet 2033. The resulting operation of the release magnet causes the wipers of the Strowger switching mechanism 1900 to be returned to rotary and vertical normal. When the relay R1950 restores, in response to the restoration of the hold relay R2010, the loop circuit extending to the called substation is interrupted to cause the restoration of the back bridge relay R2020, which latter relay, upon restoring, opens the holding circuit for the switching relay R2050. Thus, all of the relays embodied in the finder-connector link are restored to normal. Following the return of the wipers of the switching mechanism 1900 to normal, the link is entirely released and is conditioned for further use.

As explained previously, the two thermal relays 2058 and 2062 are provided for the purpose of preventing the link illustrated in Figs. 19 and 20 from being permanently appropriated to the use of a line having a calling condition thereon when no connection is established by way of the link to a called substation. More particularly, these two relays function to release the link, if the link is seized by a calling line and no impulses are transmitted thereto by way of the calling line, or if a calling subscriber fails to restore his receiver to its hook after receiving busy tone or after an established connection has been released at the called end thereof. Thus, when the link is seized, a circuit is completed for energizing the heating element 2063 embodied in the thermal relay 2062 in response to the operation of the hold relay R2010. This circuit may be traced as extending from ground at RA2011 by way of C1989, RA1913, C1982, the heating element 2063 and the resistor 2065 to battery. This circuit is maintained completed until the called line is selected, is tested, and tests idle to cause the operation of the switching relay R1910. On the other hand, if a connection is established by way of the link to a called substation, the called party releases the connection after the conversation held thereover is completed and the calling party fails to clear out the connection at the calling substation, an alternative circuit for energizing the heating element 2063 is completed, which alternative circuit may be traced as extending from ground by way of RA2021 and its associated resting contact, C1986, RA1952, C1982, the heating element 2063 and the resistor 2065 to battery. When energized over either of the two circuits just traced, the heating element 2063 transmits heat energy to the bimetallic element of the relay 2062, causing this element to be deflected to the left. After a predetermined time interval, the bimetallic element 2062 is deflected sufficiently to close the contacts 2064, thus completing a circuit by way of the resistor 2061 for energizing the heating element 2060. When the last-mentioned heating element is energized, the heat energy developed thereby causes the bimetallic strip of the relay 2058 to be deflected to the left. After a further predetermined time interval, the last-mentioned bimetallic strip is deflected a sufficient amount to cause the contacts 2059 to be opened. These springs are included in the holding circuit for the switching relay 75

R2050 so that, when opened, the last-mentioned relay restores to remove ground potential from the control conductor of the calling line and to open the loop circuit extending to the line relay R2035. The resulting restoration of the line relay R2035 is followed by the restoration of the hold relay R2010 to initiate the release of the link in the manner described previously.

If it be assumed that the calling condition responsible for seizure of the link illustrated in Figs. 19 and 20 is created on the line 33 and that the two thermal relays 2058 and 2062 operate to cause the release of the link in the manner just described, when ground potential is removed from the control conductor C1382, the cut-off relay R2260 embodied in the line circuit associated with the line 33 is deenergized and restores. Upon restoring, the relay R2260 reconnects the winding of the line relay R2250 to the calling line so that this line relay is again energized over the calling loop circuit. Upon reoperating, the line relay R2250 completes, at RA2251, a circuit extending by way of RA2256 for maintaining the slow-to-release lockout relay R2255 operated. With the lockout relay R2255 operated, the previously traced path for applying ground to the distributor switch start conductor C2328 is held open at RA2256. With the line relay R2250 operated, ground is retained on the control conductor C1382 so that the line 33 is guarded against seizure by any one of the numerical switches provided in the exchange B. Obviously, when the calling condition present on the line 33 is terminated, the line relay R2250 restores to open the holding circuit for the lockout relay R2255. When the last-mentioned relay restores, the line circuit associated with the line 33 is restored to normal.

If the permanent calling condition responsible for the seizure of the link illustrated in Figs. 19 and 20 and the operation of the two thermal relays 2058 and 2062 is present upon the line 34 rather than the line 33, the manner in which the line circuit illustrated in Fig. 31 and associated with the line 34 is operated to lock the calling line out of service is substantially similar to that just described with reference to the line circuit associated with the line 33. More particularly, when ground is removed from the control conductor C2178 at a time when a calling condition is present upon the line 34, the cut-off relay R2120 restores to reconnect the windings of the relay R2160 to the line conductors C1384 and C1386. Substantially simultaneously with the removal of ground from C2178, the holding circuit for the operated one of the lockout relays R2100 and R2110 is interrupted in the link, causing the operated lock-out relay to restore. Upon restoring, this lockout relay recomplete the circuit for energizing one of the windings of the relay R2160. Thus, if the relay R2110 is operated and restores, the upper winding of R2160 is energized, whereas, if the lockout relay R2100 is operated and restores, the lower winding of R2160 is energized. In either case, the relay R2160 re-operated to complete at RA2163 the operating circuit for R2140, which latter relay, upon re-operating, completes, at RA2143, the holding circuit for the operated slow-to-release lockout relay R2130 and applies, at RA2142, ground potential to the control conductor C1385 to maintain the line 34 marked as busy in the bank contacts of the various connector switches. With the lockout relay R2130 in its operated position, the path for applying ground to the distributor start con-

ductor C2328 is held open at RA2132 and its associated resting contact. When the calling condition present on the line 34 is terminated, the relay R2160 is deenergized and restores to open, at RA2163, the operating circuit for R2140. When the last-mentioned relay restores, it opens the holding circuit for R2130, causing the latter relay to restore after an interval to return the line circuit associated with the line 34 to normal.

SECTION 7.—TOLL CALL INITIATED AT SUBSTATION ASSOCIATED WITH LINE EXTENDING TO EX-
CHANGE B.

SUBSECTION A.—Call routed to operator's position in exchange B

If the night or transfer switch 800 provided at the operator's position illustrated in Fig. 5 occupies its restored position the operator's switching apparatus provided in the exchange B is connected for service, whereby a toll call, initiated at a substation on a line extending to the exchange B and intended for a substation associated with a line extending to one of the exchanges A, D and F, is first routed to the operator's position in the exchange B. Thus, if a calling subscriber at the substation T₁ initiates a toll call, the link illustrated in Figs. 19 and 20 is assigned to the use of the calling line and the appropriate line selecting digits of the operator's directory number are dialed, the call is forwarded to the operator's position in the exchange B. The arrangement of the connector portion of the local finder-connector link illustrated in Figs. 19 and 20 is such that, on calls of this character, the calling loop circuit is switched through to a succeeding switch or to the apparatus provided at the operator's position. More particularly, the trunk lines utilized on such calls are terminated in the contact sets forming the uppermost levels of the contact field embodied in the switching mechanism 1900 and the off-normal spring 2091 is arranged to operate from its normal position illustrated in the drawings to its off-normal position when the wipers of the switching mechanism 1900 are operated vertically to a position opposite the first of the levels terminating trunk lines of this character. Hence, when the first digit is dialed at the calling substation and during the vertical movement of the switch wipers, the spring 2091 is moved from engagement with the spring 2092 and into engagement with the spring 2093 to prepare a circuit, traced hereinafter, for energizing the lower winding of the switching-through relay R2040. During the impulses of the second digit dialed at the calling substation, the rotary magnet 1974 is energized once for each impulse and the relays R1930, R1920 and R1925 are energized and operate, all in the manner explained previously. The wipers of the switching mechanism 1900 respond to the alternating operation and restoration of the rotary magnet 1974 by traversing the contacts of the selected contact level. When the relay R1925 operates at the beginning of the first impulse of the second digit, it completes, at RA1926, the previously mentioned circuit for energizing the lower winding of R2040, this circuit extending from ground at RA2011 by way of the springs 2091 and 2093, C1984, RA1926, C1985 and the lower winding of R2040 to battery. When its lower winding is energized over this circuit, the relay R2040 only partially operates to complete at the "X" contacts associated with RA2043 a path for short-circuiting its upper winding, which path may be traced as extending from ground at RA2011 by way of

RA2043, the upper winding of R2040, C1985, RA1926, C1984 and the springs 2091 and 2093 back to ground at RA2011. At the end of the second digit dialed at the called substation, the relay R1930 is caused to restore in the manner previously explained and, upon restoring, completes, at RA1931, the test circuit for determining the idle or busy condition of the selected trunk line.

The arrangement of the local finder-connector link shown in Figs. 19 and 20 is such that automatic trunk hunting is provided with respect to the trunk lines extending to the operator's position in the exchange B. More particularly, the respective control and extra control contacts of the contact sets terminating the respective trunk lines making up the trunk line group extending to the operator's position are connected together. Also, if any particular trunk line of the group is busy, ground potential is present upon the control conductor thereof, whereas, if the line is idle, battery potential is present upon its control conductor. If it be assumed that the first trunk line of the selected group is busy, the ground potential which is present upon the test wiper 1902 results in the energization of the busy relay R1940 over the previously traced test circuit. This relay, upon operating, prepares, at RA1944, its holding circuit which is completed in response to the sequential restoration of R1920 and R1925, in the manner set forth above. At RA1943, the busy relay R1940 completes a multiple path for maintaining the upper winding of R2040 short-circuited so that this relay is prevented from completing its operation until the trunk hunting operation is ended. At RA1942, the relay R1940 opens a point in the circuit, traced previously, for energizing the upper winding of the line switching relay R1910. At RA1945, the relay R1940 short-circuits the upper winding of R1920, thereby to render the latter relay exceedingly slow to release and to insure the complete operation of R1935 before the relay R1925 restores. Immediately the wipers of the switching mechanism 1900 are moved into engagement with the contacts terminating the busy first trunk line of the selected trunk group, ground potential is impressed upon the extra control wiper 1903 to cause the energization of the relay R1935 over a circuit extending by way of RA1915, RA1928, the armature 1975, and the winding of R1935 to battery. Upon operating, the relay R1935 completes, at RA1936, a holding circuit for itself, this holding circuit extending from ground at RA2011 by way of C1989, RA1936, the armature 1975 and the winding of R1935 to battery. At RA1937, the relay R1935 completes an alternative circuit for energizing the rotary magnet 1974 in parallel with the lower winding of R1920, this circuit extending from ground at RA2014 by way of C1992 to RA1937, where it divides, one branch extending by way of RA1932 and the lower winding of R1920 to battery and the other branch extending by way of RA1918 and the winding of the magnet 1974 to battery. The continued energization of the lower winding of R1920 over the circuit just traced serves to maintain this relay operated during the trunk hunting operation. When the rotary magnet 1974 is energized over the circuit just traced, it operates to step the wipers of the switching mechanism 1900 an additional step or into engagement with the contacts terminating the next trunk line of the selected group. At its armature 1975, the rotary magnet 1974 opens a point in the pre-

viously traced holding circuit for R1935, causing this relay to restore to open an additional point in its holding circuit and to open, at RA1937, a point in the circuit, traced above, for energizing the lower winding of R1920 and the magnet 1974 in parallel. If the second trunk line of the selected group is also busy, ground potential is present upon the extra control conductor thereof so that the relay R1935 is again energized over the test circuit, traced above. Upon re-operating, this relay again completes, at RA1936, its holding circuit and, at RA1937, the circuit for energizing the lower winding of R1920 in parallel with the rotary magnet 1974. When again energized, the rotary magnet 1974 interrupts the holding circuit for R1935 and causes the wipers of the switching mechanism 1900 to be advanced into engagement with the contacts terminating the third trunk line of the selected group. The interrelated operation of R1935 and the rotary magnet 1974 continues until such time as the wipers are operated into engagement with the contacts terminating an idle trunk line of the selected group or until these wipers are moved to the position corresponding to the last line of the group. Assuming that all of the trunk lines in the group are busy, when the wipers of the switching mechanism 1900 are operated to the position corresponding to this last trunk the trunk hunting operation of the connector switch is arrested. More particularly, the control conductor of the last trunk line in the group is not connected to the extra control conductor of the set terminating this trunk line, but is left open-circuited. Hence, when the wipers are operated to the position corresponding to the last trunk line of the group, no further circuit is available for causing the reoperation of R1935 and the interrelated operation of this relay and the magnet 1974 is discontinued. Shortly thereafter, the two relays R1920 and R1925 are caused to restore in the order named and in an obvious manner. Upon restoring, the last-mentioned relay completes the previously traced holding circuit for the busy test relay R1940 and opens, at RA1926, the multiple path shunting the upper winding of the switching-through relay R1940. At RA1929, the relay R1925, upon restoring, completes the previously traced circuit for applying busy tone voltage to the calling loop circuit, thereby to signal the calling party that the desired connection cannot be obtained. Following the receipt of busy tone, the calling party may initiate the release of the operated link in the manner explained previously.

Assuming that one of the trunk lines of the selected group is idle, the movement of the wipers embodied in the switching mechanism 1900 is arrested when these wipers are rotated into engagement with the set of contacts terminating the idle line. Thus, when the wiper 1903 encounters a contact having negative battery potential thereon, the winding of R1935 is short-circuited and further operation of this relay is prevented. Also, battery potential is impressed by way of the control conductor of the idle trunk line upon the test wiper 1902 when the switch wipers encounter the set of bank contacts terminating the idle trunk line. Hence, the busy test relay R1940 is also short-circuited and restores. Shortly thereafter, the two relays R1920 and R1925 restore in the order named and in an obvious manner. With the relays R1925 and R1940 both restored, the previously traced path short-circuiting the upper winding of R2040 is

interrupted, permitting the two windings of the last-mentioned relay to be energized in series. The relay R2040 now assumes its fully operated position to open, at RA2045, a point in the circuit, traced previously, for energizing the release magnet 2033. At RA2044, the relay R2040 opens a point in the impulsing circuit extending to the rotary magnet 1974. At RA2042, the relay R2040 completes a path extending from ground at RA2011 and by way of C1987 for applying ground potential to the control conductor of the selected trunk line. At RA2041 and RA2046 and their respective associated resting contacts, the relay R2040 opens two points in the calling loop circuit, thereby to deenergize the line relay R2035. At these same armatures and their respective associated working contacts, the relay R2040 switches the calling loop circuit through to the line conductors of the selected trunk line. If it be assumed, for example, that the trunk line 36 is the first available idle line of the selected group, this trunk line is seized in the manner just described and the calling loop circuit is switched through to the line conductors thereof to complete a circuit for energizing the line relay R685 embodied in the line terminating apparatus associated with the trunk line 36 and provided at the operator's position in the exchange B. This circuit may be traced as extending from ground at the upper terminal of the lower winding of R685 by way of this winding, the transformer winding 655, C838, the switch springs 814 and 813, C882, the wiper 1904, C1995, RA2046, RA2054, the wiper 2073, C2171, RA2161, C1386, RA2101, the pulsing springs embodied in the calling device 2185, the switch springs 2166 and 2167, the receiver 2168, the transmitter 2169, the winding of R2110, RA2112, RA2111, RA2164, C2179, the wiper 2071, RA2051, RA2041, C1981, the wiper 1901, C850, the switch springs 807 and 808, C836, the transformer winding 654 and the upper winding of R685 to battery. When energized over this circuit, the relay R685 operates to complete, at RA687, an obvious circuit for energizing the slow-acting hold relay R690 and to complete, at RA686, a circuit for energizing the line signal lamp 679 in series with the relay R520. More particularly, the last-mentioned circuit extends from ground by way of RA686, RA696, the filament of the signal lamp 679, C544 and the winding of R520 to battery. The resulting illumination of the lamp 679 serves to indicate to the operator that a calling condition is present upon the trunk line 36. The visual signal indication given by the lamp 679 is supplemented by the operation of the audible signal device 525 providing the key operated switch comprising the springs 513 occupies its off-normal position. More particularly, if the springs 513 are closed, the relay R520, upon operating in response to its energization in series with the signal lamp 679, completes, at RA521, a circuit extending by way of the armature 526 for energizing the buzzer 525. The resulting operation of this buzzer indicates to the operator that an incoming call awaits attention. When the slow-to-release hold relay R690 operates in response to operation of the line relay R685, it prepares at RA692 a circuit for energizing the relay R695. At RA691, the relay R690 completes a path extending by way of C837 and the switch springs 811 and 810 for applying ground potential to the control conductor C851 of the trunk line 36. The application of ground potential to this control conductor serves to hold

the finder-connector link of Figs. 19 and 20 in its operated position independently of the line and hold relays embodied in the link. More particularly, this ground potential is forwarded by way of the wiper 1902, C1987 and RA2042 to the conductor C1989; thereby to maintain the relays R2040 and R2050 energized independently of the line and hold relays R2035 and R2010, respectively. In this regard, it will be noted that, immediately the switching-through relay R2040 operates, it opens the loop circuit to the line relay R2035. Upon restoring, this line relay opens, at RA2036, the operating circuit for the hold relay R2010. Shortly after ground is returned over the control conductor of the selected trunk line, the hold relay R2010 restores to open, at RA2011, the multiple path for applying ground potential to the conductor C1989. At RA2015, the relay R2010, upon restoring, prepares a point in the above-traced circuit for energizing the release magnet 2033, this circuit now being held open at the operated armature RA2045 of the switching-through relay R2040.

In order to answer the call, the operator in the exchange B first operates the answer switch 666 to its off-normal position, thereby operatively to associate her telephone set with the loop circuit extending to the calling substation. Thus, when the switch 666 is operated to the off-normal position, the contact springs 668 and 672 are closed to connect the series connected windings 503 and 504 of the induction coil 502 across the line terminals of the windings 651 and 652 embodied in the repeating transformer 650. Operation of the switch 666 to its off-normal position also results in the completion of a circuit for energizing the transmitter 500 embodied in the operator's telephone set, which circuit may be traced as extending from ground by way of the switch springs 667, C546, the transmitter 500, the induction coil winding 505 and the winding of the retard coil 507 to battery. It will be understood that, due to the coupling between the winding 505 and the series connected windings 503 and 504 of the induction coil 502, voice frequency currents developed by the operation of the transmitter and traversing the closed circuit, just traced, cause corresponding induced voltages to be developed in the windings 503 and 504 which are impressed upon the windings 651 and 652 of the repeating transformer 650. Similarly, signal currents traversing the windings 654 and 655 of the repeating transformer 650 cause induced voltages to be developed in the two windings 651 and 652 which are impressed by way of a circuit including the line conductors C547 and C548 and the condenser 506, upon the terminals of the receiver 501. When the answer switch 666 is operated to its off-normal position in the manner just described, an obvious circuit is completed, at the springs 670, for energizing the busy lamp 698, which lamp, in its illuminated condition, indicates that the trunk line 36 is in a busy condition. Operation of the switch 666 to its off-normal position also results in the energization and operation of R695 over a circuit extending from ground by way of the springs 671, RA692 and the winding of R695 to battery. When energized over this circuit, the relay R695 operates to open, at RA696, a point in the circuit, traced above, for energizing the line signal lamp 679 in series with the relay R520. Thus, operation of the buzzer 525 is arrested, and the lamp 679 is extinguished.

Upon conversing with the calling party, the 75

operator may ascertain the subscriber or substation desired by the calling party and take the proper steps to cause the desired connection to be established. In this regard, it is pointed out that the operator in the exchange B may route the connection to an operator's position in the exchange A or, by seizing the proper outgoing trunk line and dialing the proper line selecting digits, cause a connection to be routed directly to a substation associated with a line terminating at the exchange F, a substation associated with a line terminating at the exchange C, a substation associated with a line terminating at the exchange D, or a substation associated with a line terminating at the exchange E.

SUBSECTION B.—Extension of the connection to a substation line terminating at the exchange A

If the call initiated at the substation T₁ and 20 routed to the operator's position in the exchange B is to be extended to a substation associated with a line terminating at the exchange A, the operator who answers the call may cause the connection to be forwarded by seizing an idle trunk extending to the exchange A. For example, if the inter-office trunk line 12 is idle, the operator who answers the call may operate the call and answer switch 619 to its off-normal position, thereby to seize this trunk and to cause 25 a signal to be transmitted to the line terminating apparatus 10_a illustrated in Fig. 4 and located in the exchange A. More particularly, when the switch 619 is operated to its off-normal position, the springs 620 and 628 are closed to connect the operator's telephone set across the windings 601 and 602 of the repeating transformer 600. At the springs 625, a multiple circuit, similar to that traced previously, is completed for energizing the transmitter 500. At the springs 624, a multiple 30 circuit is completed for energizing the normally energized slow-to-release relay R635. At the springs 626, an obvious circuit is completed for energizing the line busy lamp 648.

As pointed out previously, with the arrangement illustrated, it is contemplated that, during 45 the day when an operator is on duty in the exchange B, the transfer switch 483, embodied in the line terminating apparatus illustrated in Fig. 4, shall be operated to its off-normal position, whereby conventional manual ringing may be utilized in signaling over the trunk line 12 between the two operators' positions. With this arrangement, the operator may actuate the ringing key 632 to its off-normal position to cause 50 alternating ringing current to be projected over the trunk line 12 to the apparatus 10_a. More particularly, when the switch 632 is moved to its off-normal position, an obvious circuit is completed at the springs 643 for energizing the slow-to-operate relay R645, which relay, upon operating, connects the opposite terminals of the ringing current generator, not shown but provided in the exchange B, to the line conductors C413 and C414 of the trunk line 12. When the relay R645 operates, the alternating current relay R470 is energized over a circuit which may be traced as extending from one terminal of the ringing current generator by way of the springs 633, RA646, C834, the springs 802 and 801, C413, RA496, the transformer winding 476, the winding of R470, the condenser 478, the transformer winding 471, RA408, C414, the springs 804 and 805, C835, RA647, and the springs 634 to the opposite terminal of the ringing current generator. When energized over this circuit, the 55 60 65 70 75

relay R470 operates to complete, at RA472, a circuit extending by way of RA458 and RA454 for energizing the lower winding of the relay R450. The last-mentioned relay is of the two-step type, such that it operates to close only the "X" contacts associated with RA453 in response to the energization of its lower winding. When these contacts are closed, a path is completed for short-circuiting the upper winding of R450, which path may be traced as extending from ground at RA472 by way of RA458, RA454, the upper winding of R450, RA453 and the switch springs 487 and 488 back to ground at RA461. It will be understood that the operator located in the exchange B only momentarily operates the non-locking ringing key 632 to its off-normal position and, hence, only a pulse of ringing current is transmitted over the trunk line 12 to cause the energization and operation of the relay R470. When the ringing key 632 is restored to normal, the relay R645 is caused to restore to open the above-traced circuit traversed by the ringing current and to connect the line conductors of the trunk line 12 to the line terminals of the windings 604 and 605, embodied in the repeating transformer 600. At the end of the ringing operation and when the switch 632 is restored to normal, the relay R470 is deenergized and restores to open, at RA472, a point in the previously traced path short-circuiting the upper winding of R450, permitting the two windings of the last-named relay to be energized in series over a circuit extending from ground at RA461 by way of the switch springs 486 and 487, RA453 and the two windings of R450 to battery. When its two windings are energized in series over the circuit just traced, the relay R450 completes its operation to open, at RA454, a further point in its operating circuit and to prepare at RA454 and its associated working contact, a circuit, traced hereinafter, for energizing the lower winding of R455. At RA451, the relay R450 opens a point in the circuit, traced hereinafter, for energizing the supervisory lamp 493. At RA452, the relay R450, upon fully operating, completes a circuit for energizing the line signal lamp 492, this circuit extending from ground at RA461 by way of RA452 and the filament of the lamp 493 to battery. The resulting illumination of the lamp 493 indicates to the operator on duty at the position 10 in the exchange A and having access to the equipment 10a, that an incoming call on the trunk line 12 awaits attention.

To answer the call, the operator inserts the plug terminating the conductors of her telephone set in the answer jack 482 and, in so doing, applies battery potential to the sleeve contact of the answer jack 482 to complete a circuit for energizing the relay R460, this circuit extending from ground at the upper terminal of the winding of R460 by way of this winding, and RA407 to battery as impressed upon the sleeve contact of the answer jack 482. Upon operating, the relay R460 completes, at RA463, an obvious holding circuit for itself and prepares, at RA464, a point in the pulsing circuit, traced hereinafter, for energizing the pulsing relay R410. At RA461 and its associated resting contact, the relay R460, upon operating, opens a point in the circuit, traced above, for energizing the line lamp 493, thereby to extinguish this lamp. At RA461, the relay R460 also interrupts the above-traced circuit for energizing the two windings of R450 in series, causing the latter relay to restore. 70 75

When the operator in the exchange A inserts her answer plug in the jack 482, the line terminals of her telephone set are connected, in the usual manner, across the winding 480 of the repeating transformer 475 through the tip and ring contacts of the jack 482, thereby to complete a talking connection extending by way of the trunk line 12 to the calling operator's position in the exchange B. After instructing the answering operator in the exchange A as to the party desired by the calling subscriber at the substation T1, the operator in the exchange B may establish a bridge or jumper connection between the trunk lines 36 and 12 and release the call and answer link line 553 and its associated equipment for further use. To this end, and if the connecting link line 552 is used, the two switches 607 and 658 are operated to their respective off-normal positions and the call and answer switches 619 and 666 are restored to normal. When the switch 658 is operated to its off-normal position, the springs 664 and 659 are closed to connect the line terminals of the repeating transformer windings 651 and 652 to the link line conductors C688 and C689. Similarly, when the switch 607 is operated to its off-normal position, the springs 609 and 617 are closed to connect the line terminals of the repeating transformer windings 601 and 602 to the link line conductors C688 and C689. Thus, a bridging connection including the link line 552 is completed between the trunk lines 36 and 12. When the switch 658 is operated to its off-normal position, a multiple circuit is completed at the springs 661 for maintaining the busy lamp 698 energized, and a multiple holding circuit is completed at the springs 660 for maintaining the relay R695 operated. At the springs 663, an alternative circuit, traced hereinafter, is prepared for energizing the supervisory lamp 511. When the switch 607 is operated to its off-normal position the springs 610 and 611 are closed to prepare a circuit, traced hereinafter, for energizing the relay R640. Following operation of the two switches 607 and 658 to the off-normal position, the desired bridging connection between the trunk lines 12 and 36 is completed and the link line 553 may be released. To this end, the switches 619 and 666 are restored to normal. When the key controlled switch 619 is returned to normal, the springs 620 and 628 are opened to disconnect the line conductors C547 and C548 from the windings of the repeating transformer 600. Similarly, when the switch 666 is returned to normal, the line conductors of the link line 553 are disconnected from the windings of the repeating transformer 650. At the springs 625, the multiple circuit for energizing the transmitter 500 is opened, the operating circuit for the transmitter being interrupted at the springs 667 when the switch 666 is restored to its normal position. At the springs 626, the multiple circuit for energizing the busy lamp 648 is interrupted and, at the springs 624, the multiple holding circuit for R635 is opened. Similarly, when the switch 666 is restored to normal, the multiple holding circuit for R695 is opened at the springs 671 and the multiple circuit for energizing the busy lamp 698 is interrupted at the springs 670. 60 65

After the information concerning the substation desired by the calling party is relayed from the operator in the exchange B to the operator in the exchange A, the last-mentioned operator may cause the connection to be forwarded to the desired substation line in the manner conventionally followed in manual office practice.

When the desired connection is fully established, the supervision of the calling end thereof is under the control of the operator located in the exchange B. Thus, when the call is cleared out at the calling substation T₁ and the calling loop circuit is interrupted, the line relay R685 is de-energized and restores. Upon restoring, the relay R685 opens, at RA687, the operating circuit for the slow-acting hold relay R690 and completes, at RA686, the above-mentioned circuit for energizing the supervisory signal lamp 511, this latter circuit extending from ground by way of RA686, the switch springs 663, C543, the filament of the lamp 511 and the winding of R530 to battery. The resulting illumination of the supervisory lamp 511 indicates to the operator in the exchange B that the connection routed by way of the link line 552 has been cleared out at the calling substation. If the key controlled switch comprising the springs 513 occupies its normal position at the time the line relay R685 restores, the operation of the relay R530 resulting from its energization in series with the supervisory lamp 511 causes the buzzer 535 to operate and supplement the visual signal with an audible signal. Thus, if the springs 513 are closed, the relay R530, upon operating, completes, at RA531, a circuit extending by way of the springs 513 and the armature 536 for energizing the operating magnet of the buzzer 535. In order to release the link line 552 utilized in the connection, it is only necessary for the operator in the exchange B to restore the key controlled switches 607 and 658 to normal. When the switch 607 is returned to its normal position, the line terminals of the repeating transformer windings 601 and 602 are disconnected from the link line conductors C688 and C689 and the circuit for energizing the busy lamp 648 is interrupted at the springs 613. Similarly, when the switch 658 is restored to normal, the line terminals of the repeating transformer windings 651 and 652 are disconnected from the link line conductors C688 and C689 and the circuit for energizing the busy lamp 698 is interrupted at the springs 661. Also, when the last-mentioned switch is operated to its normal position, the springs 663 are opened to interrupt the circuit, traced above, for energizing the supervisory lamp 511 in series with the relay R530, causing the lamp 511 to be extinguished and the relay R530 to restore to arrest the operation of the buzzer 535. At the springs 660, the holding circuit for the relay R695 is interrupted when the switch 658 is returned to its normal position. Upon restoring, the relay R695 reprepares, at RA696, the circuit, traced above, for energizing the line signal lamp 679.

When the hold relay R690 restores in response to the restoration of R685, it opens, at RA691, a point in the path, traced previously, for applying ground potential to the control conductor C851 of the trunk line 36. The removal of ground potential from this control conductor results in the deenergization and restoration of the two operated relays R2040 and R2050 embodied in the finder-connector link illustrated in Figs. 19 and 20. When the relay R2040 restores it initiates the release of the link in the manner described previously. Thus, the relay R2040, upon restoring, completes at RA2046 the previously traced circuit for energizing the release magnet 2033, which magnet, upon operating, causes the wipers of the switching mechanism 1900 to be returned to rotary and vertical nor-

mal in the usual manner. The manner in which the line circuit associated with the calling line is returned to normal is exactly the same as described previously.

5 In order to inform the operator in the exchange A that the connection has been cleared out at the calling end thereof, the operator in the exchange B momentarily operates the ringing key 632 to its off-normal position to cause ringing current to be projected over the trunk line 12. This current traverses the two windings 476 and 477 causing the corresponding voltage to be induced in the winding 480, which voltage serves to energize a ring up relay conventionally provided in the operator's cord circuit. The resulting operation of this relay serves to energize a visual or audible signal associated with the cord circuit, thereby to indicate to the operator at the position 10 in exchange A that the connection may be released. It will be noted that the two relays R470 and R450 respond to the pulse of ringing current transmitted over the trunk line 12 for the purpose of signaling the operator in the exchange A. Since the relay R460 is operated at this time, however, the momentary operation of the two relay R470 and R450 is without effect. Upon receiving the disconnect signal, the operator in the exchange A may initiate the release of the established connection extending to the called subscriber's substation in the usual manner. During the release operation, the operator withdraws the plug terminating the conductors of her telephone set from the answer jack 482, thereby interrupting the circuit over which R460 is being held energized. Following the restoration of R460, the apparatus illustrated in Fig. 4 is in its normal condition and is prepared for further use.

40 *SUBSECTION C.—Extension of the connection to a substation line terminating at the exchange A, C, D, E, or F when the operator in exchange B is off duty*

45 As explained previously, when the operator in the exchange B leaves her position or goes off duty, the transfer switch 800 is operated to its off-normal position so that the springs thereof assume the positions illustrated in the drawings. Also, the transfer switch 483 located at the operator's position in the exchange A is operated to a position such that the springs embodied therein occupy the positions illustrated in the drawings. With the transfer switch 800 occupying its off-normal position, all calls intended for the operator's position in the exchange B are automatically forwarded to an operator's position in the exchange A. Thus, if the call described in the preceding subsection and originating at the substation T₁ is initiated at a time when the transfer switch 800 occupies its off-normal position, the calling loop circuit is switched through to the repeater illustrated in Figs. 10 and 11 in response to the switching-through operation of the connector switch of Figs. 19 and 20 which occurs following the seizure of the trunk line 36. When the calling loop circuit is switched through to the repeater of Figs. 10 and 11, the line relay R1005 embodied therein is energized over a circuit which may be traced as extending from ground at the upper terminal of the lower winding thereof, by way of this winding, C845, the switch springs 815 and 813, C852, the switch wiper 1904, C1995, RA2046, RA2054, the wiper 2073, C2117, RA2161, RA2101, the pulsing springs 75 embodied in the calling device 2185, the switch

springs 2166 and 2167, the receiver 2168, the transmitter 2169, the winding of R2110, RA2112, RA2111, RA2164, C2179, the switch wiper 2071, RA2051, RA2041, C1981, the wiper 1901, C850, the switch springs 807 and 809, C843 and the upper winding of R1005 to battery. Upon operating, the relay R1005 completes, at RA1006, an obvious circuit for energizing the slow-acting hold relay R1000. The relay R1000, upon operating, completes, at RA1001, an obvious path for applying ground to the control conductor C844, which ground is extended by way of the switch springs 812 and 810 to the control conductor C851 of the trunk line 36, thereby to maintain the link illustrated in Figs. 19 and 20 operated after the line and hold relays embodied therein restore in the manner previously explained. At RA1003, the relay R1000, upon operating, prepares a circuit, traced hereinafter, for energizing the relay R1030. At RA1002 and its associated working contact, the relay R1000 completes a circuit for energizing the slow-acting relay R1100, this circuit extending from ground by way of RA1002, RA1036, C1082, RA1112 and the winding of R1100 to battery. When energized over this circuit, the relay R1100 operates to prepare, at RA1104, a circuit for energizing the slow-to-operate relay R1105; to complete, at RA1103, a circuit extending from ground at RA1133 for energizing the slow-acting relay R1120; and to complete at RA1102 a circuit extending from ground at RA1132 for energizing the relay R1140. The relay R1140, upon operating, completes, at RA1142, the above-mentioned circuit for energizing the slow-to-operate relay R1105. At RA1141 and RA1143 and their respective associated working contacts, the relay R1140 connects the opposite terminals of the alternating current source, not shown, but provided in the exchange B to the line conductors C841 and C842 of the trunk line 28, which trunk line is now connected by way of the springs of the transfer switch 800 to the trunk line 12 extending to the operator's position 10 in the exchange A. At its armatures RA1121 and RA1122, the slow-acting relay R1120, upon operating, disconnects the line terminals of the repeating transformer windings 1178 and 1179 from the line conductors of the trunk line 28, thereby to prevent alternating current from being fed back over the calling loop circuit to the calling substation. The relay R1105, upon operating, completes, at RA1107, an obvious circuit for energizing the relay R1110. At RA1109, the relay R1105 completes a circuit for energizing the relay R1030, this circuit extending from ground by way of RA1109, C1094, RA1003 and the winding of R1030 to battery. The relay R1030, upon operating, completes, at RA1038, a holding circuit for itself, which holding circuit extends from ground at RA1057 by way of RA1038 and the winding of R1030 to battery. At RA1032, the relay R1030 prepares an alternative path for applying ground potential to the control conductor C844 of the trunk line 40. At RA1031 and RA1039, the relay R1030 connects the line conductors C843 and C845 of the trunk line 40 through to the line terminals of the repeating transformer windings 1174 and 1175. At RA1036, the relay R1030 opens a point in the above-traced operating circuit for the relay R1100 causing the last-mentioned relay to restore. A further point is opened in the operating circuit for R1100 in response to the operation of R1110, which latter relay operates substantially simultaneously with the operation of R1030. Upon restoring, the re-

lay R1100 opens, at RA1104, the above-traced operating circuit for R1105, causing the last-mentioned relay and the relay R1110 to restore in the order named. At RA1102 and RA1103, respectively, the relay R1100 opens the respective operating circuits, traced previously, for the two relays R1120 and R1140, causing both of these relays to restore. When the two last-mentioned relays fall back, the line conductors C841 and C842 are disconnected from the alternating current source and are reconnected to the line terminals of the repeating transformer windings 1178 and 1179.

From the foregoing description, it will be apparent that the relays R1100, R1140, R1110, and R1030 cooperate to cause a seizing pulse of alternating current to be transmitted by way of the trunk line 12 to the operator's position 10 in the exchange A. The duration of this pulse is primarily determined by the slow-acting characteristics of the two relays R1100 and R1105 and is relatively short. The path traversed by the alternating current may be traced as extending from one terminal of the alternating current source, not shown, by way of RA1141, C841, the switch springs 803 and 801, C413, RA406, the transformer winding 476, the winding of R470, the condenser 478, the transformer winding 477, RA408, C414, the switch springs 804 and 806, C842 and RA1143 to the opposite terminal of the alternating current source. When energized over this circuit, the alternating current relay R470 operates, in the manner explained above, to complete, at RA472, the previously traced circuit for energizing the lower winding of R450. The last-mentioned relay, upon partially operating, completes, at the "X" contacts associated with RA453, an alternative path for short-circuiting its upper winding, which path may be traced as extending from ground at RA434 by way of the switch springs 488 and 487, RA453, the upper winding of R450, RA454, and RA458, back to ground at RA472. The alternating current relay R470, upon operating, also opens, at RA471, a point in the path by way of which signal currents are transmitted to the operator's telephone set, thereby to preclude the possibility of the operator's receiver being energized by the alternating current.

At the end of the seizing pulse of alternating current transmitted by way of the trunk line 12 and when the relay R1140 restores in the manner just explained, the alternating current relay R470 is deenergized and restores to open, at RA472, a point in the above-traced path short-circuiting the upper winding of R450, permitting the two windings of this relay to be energized in series. The relay R450 now completes its operation to complete, at RA452, the previously traced circuit for energizing the line signal lamp 493. At RA451, the relay R450 opens a point in the circuit for energizing the supervisory lamp 492 and, at RA454, it opens a point in its operating circuit and prepares a point in the operating circuit for the relay R455.

The illuminated condition of the line signal lamp 493 indicates to the operator at the position 10 in the exchange A that a call is present on the trunk line 12 which should be answered. To answer the call, the operator inserts the plug terminating the line conductors of her telephone set in the answer jack 482 in the manner explained previously. In response to this operation, the relay R460 operates to complete its holding circuit and to open at RA461 and its

associated resting contact the circuit for energizing the line signal lamp 493. At RA462, the relay R460 completes a holding circuit for R450, which circuit may be traced as extending by way of RA466, the switch springs 488 and 487, RA453 and the two series connected windings of R450 to battery. At RA461 and its associated working contact, the relay R460 completes a circuit for energizing the slow-to-operate relay R445 in parallel with the relay R405, one branch of the circuit extending by way of the switch springs 484, RA416, RA422 and the winding of R445 to battery, and the other branch of the circuit extending by way of the switch springs 484, RA436 and the winding of R405 to battery. The relay R405, upon operating, completes, at RA406 and RA408 and their respective associated working contacts, a circuit for projecting alternating current over the trunk line 12 to the repeater illustrated in Figs. 10 and 11. At RA401, the relay R405 opens a point in the above-traced operating circuit for R460. When energized over the circuit traced above, the relay R445 operates, after an interval, to prepare, at RA447, an alternative circuit, traced hereinafter, for energizing the relay R405 and to complete, at RA446, an obvious circuit for energizing the slow-to-release relay R430. The last-mentioned relay, upon operating, completes at RA432, a circuit extending by way of RA438 and its associated resting contact for energizing the relay R440. The relay R440 now operates to complete, at RA441, RC442 and RC443, an obvious circuit for energizing the slow-to-operate relay R433. The last-mentioned relay, upon operating, completes, at RA439 an obvious holding circuit for itself; prepares, at RA439', a circuit for energizing the pulsing relay R410; opens, at RA434, the multiple holding circuit for R450; opens, at RA436, a point in the above-traced operating circuit for R405; and completes, at RA437, a holding circuit for R440, which latter circuit may be traced as extending from ground at RA461 by way of the switch springs 484, RA431, RA438 and the winding of R440 to battery. When its operating circuit is interrupted in the manner just described, the relay R405 restores to terminate the pulse of alternating current transmitted by way of the trunk line 12 to the repeater illustrated in Figs. 10 and 11. Also, upon restoring, the relay R405 reconnects the line conductors C413 and C414 of the trunk line 12 to the line terminals of the repeating transformer windings 476 and 477.

When the alternating current source provided in the exchange A is connected to the line conductors of the trunk line 12, the relay R1115 embodied in the repeater illustrated in Figs. 10 and 11 is energized over a circuit which may be traced as extending from one terminal of the ringing current source by way of RA411, RA406, C413, the switch springs 801 and 803, C841, RA1141, RA1121, the winding 1178, the condenser 1177, the winding of R1115, the winding 1179, RA1122, C842, the switch springs 806 and 804, C414, RA408, and RA412 to the opposite terminal of the alternating current source. The relay R1115, upon operating, opens, at RA1116, a point in the calling loop circuit, thereby to prevent the alternating ringing current from being transmitted to the calling substation. At RA1117, the relay R1115 completes a circuit for energizing the lower winding of R1012, this circuit extending from ground by way of RA1117, C1090, RA1037' and its associated working contact, RA1023, RA1017 and the lower winding of

R1012 to battery. When its lower winding is energized over this circuit, the relay R1012 partially operates to complete, at the "X" contacts associated with RA1013, a path for short-circuiting its upper winding, this path extending from ground at RA1033 by way of RA1041, RA1013, the upper winding of R1012, RA1017, RA1023, RA1037' and C1090 back to ground at RA1117. At the end of the pulse transmitted by way of the trunk line 12 to the repeater illustrated in Figs. 10 and 11, the relay R1115 restores to open, at RA1117, the above-traced path short-circuiting the upper winding of R1012 and to recomplete, at RA1116, the calling loop circuit. When the short-circuiting path, traced above, is interrupted, the two windings of R1012 are energized in series and this relay completes its operation to prepare, at RA1017, a circuit, traced hereinafter, for energizing the lower winding of the relay R1020. At RA1014 and RA1015, the relay R1012 reverses the polarity of the battery voltage impressed upon the line conductors C1551 and C1553 of the trunk line 44 through the windings of the line relay R1005, but such voltage polarity reversal is without effect in the case here being considered. It will be noted that the polarity of the battery voltage impressed upon the line conductors C843 and C845 of the trunk line 40 through the windings of the line relay R1005 is not affected by the operation of the relay R1012.

Following the operation and restoration of the alternating current relay R1115 in response to the pulse of alternating current transmitted over the trunk line 12 in the manner just described, the desired conversational connection between the calling substation T₁ and the operator's telephone station in the exchange A is fully completed. If the substation desired by the calling party is associated with a line terminating at the exchange A, the operator may forward the connection to the desired substation in the manner conventionally followed in manual office practice. On the other hand if the call is to be forwarded to a line terminating at one of the exchanges C, D, E or F, the operator in the exchange A may cause the desired connection to be set up in the manner explained subsequently in section 9, subsections B and D. At the end of the conversation and when the connection is cleared out at the calling substation T₁, the calling loop circuit is interrupted, in the usual manner, causing the line relay R1005 to restore. Upon restoring, the relay R1005 opens, at RA1006, the operating circuit for the hold relay R1000, which latter relay, upon restoring, completes, at RA1001, the above-mentioned alternative path for maintaining ground on the control conductor C844, this path extending from ground at RA1032 by way of RA1001 to the control conductor noted. At RA1007, the relay R1005, upon restoring, completes an alternative circuit for energizing the relay R1120, which circuit may be traced as extending by way of RA1031, C1083 and the winding of R1120 to battery. The relay R1120, upon operating, disconnects the line terminals of the repeating transformer windings 1178 and 1179 from the line conductors C841 and C842 of the trunk line 28. At RA1006, the relay R1005 also completes an alternative circuit for energizing the relay R1140, this circuit extending from ground by way of RA1006, RA1035, C1080 and the winding of R1140 to battery. When energized over this circuit, the relay R1140 again connects the line

conductors of the trunk line 28 to the alternating current source provided in the exchange B, thereby to complete the previously traced circuit for energizing the alternating current relay R470. At RA1002 and its associated resting contact, the relay R1000, upon restoring, completes a circuit for energizing the upper winding of R1130, this circuit extending by way of RA1034, C1079 and the upper winding of R1130 to battery. Upon operating, the relay R1130 prepares, at RA1131, a circuit, traced hereinafter, for energizing the operating magnet 1072 of the rotary switch 1070; prepares, at RA1133, a circuit for energizing the slow-to-operate relay R1105; and completes, at RA1132, a circuit, extending by way of RA1112, for energizing the relay R1100. The relay R1100, upon operating, completes the previously traced circuit for energizing the slow-to-operate relay R1105 and also completes, at RA1101, a multiple holding circuit for R1130, which latter circuit may be traced as extending from ground at RA1131 by way of RA1101 and the upper winding of R1130 to battery. The relay R1105, upon operating, shunts, at RA1106, the operated armature RA1101 of the relay R1100, thereby to provide a multiple holding circuit for R1130. At RA1107, the relay R1105 completes the operating circuit for the relay R1110, which latter relay, upon operating, opens, at RA1112, the operating circuit for R1100 and completes, at RA1111, the above-mentioned circuit for energizing the operating magnet 1072 of the minor switch 1070. Upon restoring, the relay R1100 opens, at RA1104, the operating circuit for R1105, which latter relay, in turn, restores to open the operating circuit for R1110. When R1110 restores, it recompletes, at RA1112, the operating circuit for R1100, thereby to again initiate the sequential operation of R1105 and R1110. The cyclic operation of the three relays R1100, R1105 and R1110 continues until the wiper 1071 of the rotary switch 1070 is stepped to its fifth off-normal position. More particularly, during each cycle of operation of the three relays R1100, R1105 and R1110, the rotary magnet 1072 is energized in response to the operation of R1110 and is deenergized when the relay R1110 restores. The circuit for energizing the magnet 1072 may be traced as extending from ground at RA1131 by way of RA1111, C1078 and the winding of the magnet 1072 to battery. When the wiper 1071 is caused to take its first step from the normal position, the off-normal springs 1074 are closed to prepare a circuit, traced hereinafter, for energizing the release magnet 1073 of the minor switch 1070. When the wiper 1071 of the minor switch 1070 is stepped to its fifth off-normal position, the winding of the relay R1030 is short-circuited over a path extending from ground at RA1033 by way of the wiper 1071 and the two contacts engaged thereby, the winding of R1030 and RA1038 back to ground at RA1051. When its winding is short-circuited over the path just traced, the relay R1030 restores to open, at RA1031 and RA1039, two further points in the calling loop circuit and to interrupt, at RA1032, the above-traced alternative path for impressing ground potential upon the control conductor C844 of the trunk line 40. Also, the relay R1030, upon restoring, opens, at RA1035 and RA1037, the respective alternative operating circuits, as traced above, for the two relays R1140 and R1120, causing both of these relays to restore. At RA1034, the relay R1030, upon restor-

ing, opens a point in the above-traced operating circuit for R1130, permitting the last-mentioned relay to restore following the restoration of the two relays R1100 and R1105, to open the holding circuit for R1130. When the relay R1140 restores, the alternating current source provided in the exchange B is disconnected from the line conductors C841 and C842 of the trunk line 28, thereby to terminate the pulse of alternating current being transmitted over the trunk line 12 to the operator's position in the exchange A. The relay R1130, upon restoring, opens, at RA1132 and RA1133, points in the respective operating circuits for the two relays R1100 and R1105, thereby to arrest the cyclic operation of these two relays and the relay R1110. At RA1131 and its associated working contact, the relay R1130 opens a further point in its holding circuit and, at RA1131 and its associated resting contact, the relay R1130 completes a circuit for energizing the release magnet 1073 embodied in the minor switch 1070. The last-mentioned circuit may be traced as extending from ground at RA1131 by way of C1084, the closed off-normal springs 1074, and the winding of the release magnet 1073 to battery. When energized over this circuit, the release magnet operates to cause the wiper 1071 to be returned to its normal position in the usual manner, at which time the off-normal springs 1074 are opened to interrupt the operating circuit for the release magnet 1073.

From the foregoing description it will be apparent that a relatively long pulse of alternating current is impressed upon the trunk line 12 by the repeater shown in Figs. 10 and 11 in response to the release of the connection at the calling substation T1. When this alternating current release pulse is impressed upon the trunk line 12, the alternating current relay R470 is energized and operates to complete, at RA472, a circuit for energizing the lower winding of R455, this circuit extending by way of RA458, RA454 and the lower winding of R455 to battery. When its lower winding is energized over this circuit, the relay R455, which is of the two-step type, partially operates to complete, at the "X" contacts associated with RA457, a path for short-circuiting its upper winding, this path extending from ground at RA462 by way of RA466, the switch springs 488 and 487, RA457, the upper winding of R455, RA454 and RA458 back to ground at RA472. At the end of the release pulse, when the relay R1140 is caused to restore to disconnect the alternating current source from the conductors of the trunk line 12, the relay R470 restores to open, at RA472, a point in the path short-circuiting the upper winding of R455, permitting the two windings of this relay to be energized in series. The relay R455 now completes its operation to open, at RA458, a point in its operating circuit and to complete, at RA456, an obvious circuit for energizing the slow-to-operate relay R465. The last-mentioned relay, upon operating, opens, at RA466, a point in the holding circuits for each of the two relays R450 and R455, causing both of these relays to restore. The relay R455, upon restoring, opens, at RA456, the operating circuit for R465, causing the latter relay to restore. At RA451, the relay R450, upon restoring, completes a circuit for energizing the supervisory lamp 492, this circuit extending from the ground at RA461 by way of the switch springs 484, RA451 and the filament of the lamp 492 to bat-

terry. The illumination of the lamp 492 indicates to the operator that the connection has been released at the calling substation and that the trunk line utilized in the connection is ready to be released for further use. To release the 5 trunk line 12 and the equipment associated therewith, the operator withdraws her connecting plug from the answer jack 482, thereby to remove battery potential from the sleeve contact of the jack 482 to cause the deenergization 10 of the relay R460. Upon restoring, the relay R460 opens, at RA463, a point in its holding circuit; opens, at RA461, the above-traced operating circuit for the supervisory lamp 492; and completes, at RA462, a circuit extending by way 15 of RA436 for again energizing the relay R405. The relay R405 now reoperates to connect, at RA406 and RA408 and their respective associated working contacts, the conductors of the trunk line 12 to opposite terminals of the alternating current source provided in the exchange A, thus causing a pulse of alternating current to be transmitted by way of the trunk line 12 to the repeater illustrated in Figs. 10 and 11. When the relay R460 restores, it also opens, at RA461, 20 a point in the common portion of the holding circuits for the two relays R440 and R445. The relay R445, upon restoring, opens, at RA446, the operating circuit for R430, causing the latter relay to restore. When the relay R440 is deenergized, its weighted armature RA441 is released and starts vibrating alternately to make contact with its two associated contact springs 25 RC442 and RC444. During the time interval when the armature RA441 is vibrating to engage the two enumerated contacts, the relay R433 is held energized over its holding circuit. When the amplitude of vibration of RA441 is decreased so that it no longer engages RC442 and RC444, the operating and holding circuits for R433 are 30 opened and this relay restores to open, at RA436, the above-traced operating circuit for R405. The relay R405, upon restoring, disconnects the conductors of the trunk line 12 from the alternating current source provided in the exchange A, thereby to terminate the pulse of alternating current transmitted by way of this trunk line to the repeater illustrated in Figs. 10 and 11. Following the restoration of the relay R405, all of the relays illustrated in Fig. 4 are deenergized 35 and the trunk line terminating equipment shown in this figure is conditioned for further use.

When the pulse of alternating current is applied to the trunk line 12 through the operation of the relay R405 in the manner just described, 40 the alternating current relay R1115 embodied in the repeater illustrated in Figs. 10 and 11 is energized and operates to complete, at RA1117, a circuit for energizing the upper winding of R1050, this circuit extending by way of C1090, RA1037, RA1056 and the upper winding of R1050 to battery. When its upper winding is energized over this circuit, the relay R1050 partially operates to complete, at the "X" contacts 45 associated with RA1054, a path for short-circuiting its lower winding, which path may be traced as extending from ground by way of RA1054, RC1048, RA1047, the lower winding of R1050, RA1056, RA1037, and C1090 back to ground at RA1117. At the end of the alternating 50 current pulse the relay R1115 is deenergized and restores to open, at RA1117, a point in the path short-circuiting the lower winding of R1050, permitting the two windings of the last-mentioned relay to be energized in series. The relay 55

R1050 now completes its operation to open, at RA1056, a point in its operating circuit and to complete, at RA1051, RA1055 and RA1059, a loop circuit extending by way of the trunk line 29 to the incoming connector switch illustrated in Figs. 12 and 13. When this loop circuit is completed, the indicated incoming connector switch is seized and operates, in the manner described hereinafter, to condition itself to respond to impulses transmitted thereto over the trunk line 29. At RA1057, the relay R1050 completes an obvious circuit for energizing the upper winding of the differential relay R1065. The relay R1065 does not operate at this time, however, since the currents respectively traversing its two windings are differentially related. At RA1052, the relay R1050 completes a path extending by way of RA1001 for applying ground potential to the control conductor C1552 of the trunk line 44 and to the control conductor C844 of the trunk line 40, thereby to mark the repeater as busy in the numerical switches having access thereto. At RA1058, the relay R1050 completes a circuit for energizing the slow-to-release relay R1165, this circuit extending from ground at RA1058 by way of C1095, RA1171, RA1151 and the winding of R1165 to battery. When energized over this circuit the relay R1165 operates to prepare, at RA1167, a holding circuit for itself and to prepare, at RA1166, a circuit, traced hereinafter, for energizing the relay R1150.

At RA1057, the relay R1050, upon fully operating, completes a circuit for energizing the lower winding of R1130, which circuit extends by way of C1092, RA1154 and the lower winding of R1130 to battery. The relay R1130 operates when its lower winding is energized over this circuit to prepare, at RA1131, the above-traced operating circuit for the rotary magnet 1072 and a point in its own holding circuit. At RA1133, the relay R1130 prepares the previously traced operating circuit for R1105. At RA1132, the relay R1130 completes the above-described operating circuit for the slow-acting relay R1100, which latter relay, upon operating, completes at RA1104 the operating circuit for R1105, thereby to initiate the cyclic operation of the three relays R1100, R1105 and R1110 in the manner described previously. During each cycle of operation of these three relays, the operating circuit for the rotary magnet 1072 is completed in response to operation of the relay R1110, and is interrupted when the relay R1110 restores. Thus, the wiper 1071 is caused to be driven from its home position over the contacts of the associated contact set. When the wiper 1071 is driven to its ninth off-normal position, an obvious circuit is completed for energizing the slow-to-release relay R1045, which relay, upon operating, opens the holding circuit for R1050 and simultaneously completes an alternative holding circuit for this relay. This alternative circuit extends from ground at the inner ninth contact of the contact bank embodied in the rotary switch 1070 by way of the bridging wiper 1071, the outer ninth contact of the bank contact field, RA1046, RA1047 and the two windings of R1050 in series to battery. When the wiper 1071 is stepped to its tenth off-normal position the operating circuit for R1045 and the alternative holding circuit for R1050 are both interrupted, causing these two relays to restore. The relay R1050, upon restoring shortly before the relay R1045 falls back, opens, at RA1054, a further point in its original holding circuit. At RA1058, the relay R1050

opens the previously traced operating circuit for R1165 and, at RA1051, it interrupts the operating circuit for the relay R1130. RA1051, RA1055 and RA1059, the relay R1050 opens the loop circuit extending to the operated incoming connector switch illustrated in Figs. 12 and 13. The interruption of the loop circuit extending to this incoming connector switch causes the switch to be released in the manner explained in detail hereinafter. With its operating circuit interrupted, the relay R1130 is held energized over its holding circuit until the period of the next operating cycle of the three relays R1100, R1105 and R1110 when the two first-named relays are deenergized. When the relays R1100 and R1105 restore the holding circuit for R1130 is interrupted, and this relay restores to open the operating circuits for the two enumerated relays and to interrupt, at RA1131, a point in the circuit for energizing the operating magnet 1072. Thus, the cyclic operation of the three relays R1100, R1105 and R1110 is arrested. At RA1131 the relay R1130, upon restoring, completes the previously traced circuit for energizing the release magnet 1073, thereby to cause the wiper 1071 to be returned to its home position in the usual manner. Following the release of the switch 1070, the repeater illustrated in Figs. 10 and 11 is restored to normal and the connection is fully released.

SUBSECTION D.—Extension of the connection to a substation line terminating in the Exchange C when the operator in the exchange B is on duty

As pointed out previously, in the system illustrated, a call initiated at a substation associated with a line terminating at the exchange B and intended for a substation associated with a line extending to the exchange C is first routed to the operator's position in the exchange B or to the operator's position in the exchange A and from either of these two positions to the desired substation line terminating in the exchange C. Thus, if the operator in the exchange B, upon answering the call forwarded to her position from the calling substation T₁ in the manner explained in this section, Subsection A, is informed that the substation desired by the calling subscriber is associated with a line extending to the exchange C, as for example the substation T₅, she may cause the desired connection to be set up by seizing the incoming connector switch illustrated in Figs. 12 and 13 and thereafter dialing the appropriate line selecting digits. To seize the indicated incoming connector switch, the switch 764 is operated to its off-normal position. After this incoming connector switch is seized the operator may dial the directory number of the substation T₅, operate the two connecting switches 658 and 157 to establish a link connection between the calling and called talking circuits and then restore the two call and answer switches 666 and 764 to normal to disconnect her telephone set from the established talking connection. When the call and answer switch 764 is operated to its off-normal position, the line conductors C547 and C548 of the link line 553 extending to the operator's telephone set are connected, at the springs 166 and 770, to the line terminals of the repeating transformer windings 772 and 773. At the springs 768, an obvious circuit is completed for energizing the line busy lamp 763 and, at the springs 765, an obvious multiple circuit is completed for maintaining the transmitter 500

energized. At the springs 767, a circuit is prepared for energizing the control relay R780 and, at the springs 769, an obvious circuit is completed for energizing the relay R795. Upon operating, the relay R795 completes, at RA796, an obvious circuit for energizing the lower winding of R790 and completes, at RA797, a loop circuit extending to the incoming connector switch illustrated in Figs. 12 and 13, thereby to cause the energization and operation of the line relay R1235. More particularly, the line relay R1235 is energized over a circuit which may be traced as extending from ground by way of RA1254, the lower winding of R1235, the lower winding of R1230, RC1227, RA1226, RA1206, C854, the switch springs 821 and 822, RA185, RC186, the winding 776, the resistor 191', the upper winding of R790, RA797, the winding 775, RC183, RA782, the switch springs 817 and 816, C853, RA1201, RA1223, RC1224, the upper winding of R1230 and the upper winding of R1235 to battery. At this time the two windings of R790 are differentially energized and, hence, this relay does not operate. Also, the two windings of the relay R1230 are differentially energized so that this does not operate. The relay R1235, upon operating, completes, at RA1236, an obvious circuit for energizing the slow-acting hold relay R1240. The relay R1240, upon operating, opens, at RA1244, a point in the circuit, traced hereinafter, for energizing the release magnet 1208; prepares, at RA1243, an impulsing circuit for energizing the vertical and rotary magnets 1256 and 1356, respectively; and completes, at RA1242, a circuit extending by way of the off-normal springs 1255 for energizing the upper winding of the slow-acting relay R1245. The relay R1245 now operates further to prepare, at RA1247, the circuit for energizing the vertical magnet 1256. At RA1246, the relay R1245 completes an obvious circuit for energizing the relay R1250. Upon operating, the relay R1250 completes, at RA1251, a path for applying ground potential to the ringing and tone apparatus start conductor C1251', this path extending from ground at RA1221 by way of C1263, RA1312, C1264 and RA1251 to the start conductor C1251'. When ground is applied to this start conductor, the operation of the ringing and tone apparatus provided in the exchange B is initiated in the usual manner. At RA1253 and RA1254, the relay R1250, upon operating, includes the secondary winding 1259 of the transformer 1258 in the calling loop circuit. Thus, dial tone current is caused to flow over the calling loop circuit and through the windings 775 and 776 of the repeating transformer 771 so that the usual dial tone signal is reproduced by the operator's telephone receiver 501.

Upon receiving dial tone, the operator may operate the calling device 508 in accordance with the directory number designating the called substation T₆. During each back stroke of the dial embodied in the calling device 508, the shunt springs 509 are closed to complete an obvious circuit for energizing the slow-to-release relay R540, which relay, upon operating, completes a circuit for energizing the relay R780. The last-mentioned circuit extends from ground by way of the shunt springs 509, RA542, C549, the switch springs 767 and the winding of R780 to battery. When energized over this circuit, the relay R780 operates to connect, at its armature springs RA781, RA782, RA784 and RA785, the impulsing springs 510 of the calling device 508 directly across the line conductors C853 and C854 of the

trunk line 30 extending to the incoming connector switch shown in Figs. 12 and 13. At RA1782 RA1785 and their respective associated contacts RC1783 and RC1786, the relay R180 disconnects the line terminals of the repeating transformer windings 715 and 716 from the line conductors C853 and C854 of the trunk line 30. At the end of each digit and when the dial of the calling device 508 restores to normal, the shunt springs 509 are opened to cause the restoration of the two relays R540 and R180. When the relay R180 restores it recomplete the initially established loop circuit extending to the operated incoming connector switch. During each back stroke of the dial embodied in the calling device 508, the impulsive springs 510 are opened a number of times determined by the number of impulses making up the digit dialed, so that the loop circuit extending to the incoming connector switch illustrated in Figs. 12 and 13 is interrupted in accordance with the impulses of the digit. Each time this loop circuit is interrupted, the line relay R1235 restores to complete, at RA1236, the previously mentioned circuit for energizing the vertical magnet 1256, this circuit extending from ground by way of RA1236, RA1243, RA1247 and the winding of the magnet 1256 to battery. It will be noted that the lower winding of the relay R1245 is also energized over the impulsive circuit just traced. Each time the vertical magnet 1256 is energized, it operates to elevate the wipers 1371 to 1374, inclusive, of the Strowger switching mechanism 1370 one step in a vertical direction. Accordingly, at the conclusion of the first digit, the enumerated wipers are left standing opposite the level of bank contacts corresponding to the number of impulses making up the digit. When the enumerated wipers are moved the first step in the vertical direction, the off-normal springs 1255 are opened to interrupt the above-traced circuit for energizing the upper winding of R1245; the off-normal springs 1257 are closed to complete an obvious multiple path for maintaining ground on the ringing and tone apparatus start conductor C1251'; and the off-normal springs 1207 are closed to prepare a circuit, traced hereinafter, for energizing the release magnet 1208. Due to its slow-to-release characteristic, the relay R1245 is held operated for the duration of the digit through the repeated energization of its lower winding over the impulsive circuit as traced above. At the end of the first digit, the line relay R1235 is maintained operated for a sufficient time interval to permit the relay R1245 to restore. Upon restoring, the last-mentioned relay opens, at RA1247, the circuit for energizing its own lower winding and the winding of the magnet 1256 in parallel and interrupts, at RA1246, the operating circuit for the relay R1250. When the relay R1250 restores, it opens, at RA1251, the original path for applying ground potential to the ringing and tone apparatus start conductor C1251' and excludes, at RA1253 and RA1254, the secondary winding 1259 of the dial tone transformer 1258 from the calling loop circuit.

The arrangement of the control apparatus embodied in the incoming connector switch, shown in Figs. 12 and 13, is similar to that of the local connector switch illustrated in Figs. 19 and 20 and described previously, in that its operation is different depending upon the character of the line to be selected. More particularly, the arrangement of the incoming connector switch of Figs. 12 and 13 is such that the switch is adapted

to seize a subscriber's line of the single party, duplex or multiplex type, or to seize a trunk line extending to a succeeding automatic switch or repeater, the different modes of operation being determined by the number of impulses making up the first series of impulses transmitted to the switch. The manner in which the incoming connector switch illustrated in Figs. 12 and 13 operates when a connection is to be extended to a line of the single party, duplex or multiplex type, is described hereinafter in Section 9, Subsection A. In the present case, the repeater illustrated in Figs. 17 and 18 and terminating the trunk line 32 is assumed to be one of a group of similar repeaters individually terminating trunk lines extending to the exchange C. These trunk lines are terminated in a particular level of the bank contacts embodied in the Strowger mechanism 1370, and the arrangement of the control apparatus embodied in the incoming connector switch is such that automatic trunk hunting is provided for the purpose of selecting an idle trunk in the group. Also, the arrangement is such that the calling loop circuit is switched through to the repeater terminating the selected idle trunk line when the trunk hunting operation is terminated.

In the case here being considered, wherein a trunk line in the group including the line 32 is to be selected, the off-normal springs 1216 are closed during the vertical movement of the wipers 1371 to 1374, inclusive, to prepare a circuit for energizing the switching-through relay R1200. Following the dialing of the first or group selecting digit, the operator in the exchange B dials the particular digit identifying the group of trunk lines including the line 32. During each impulse of this digit the line relay R1235 restores to complete the above-mentioned circuit for energizing the rotary magnet 1356 in series with the slow-acting relay R1335, this circuit extending from ground at RA1236 by way of RA1243, RA1247, RA1204, C1272, RA1326, the winding of R1335, RA1366 and the winding of the magnet 1356 to battery. A branch of this circuit extends by way of RA1337 and through the upper winding of the relay R1340 to battery, whereby the relays R1340 and R1335 are both caused to operate at the beginning of the first impulse of the second digit. Upon operating, the relay R1335, at RA1337, opens the operating circuit for R1340 and completes a holding circuit therefor. At RA1336, the relay R1335 opens a point in the circuit, traced hereinafter, for energizing the lower winding of the busy test relay R1320. The relay R1340, upon operating, opens, at RA1341, a point in the operating circuit for the slow-to-operate relay R1360 and completes, at RA1342, an obvious circuit for energizing the relay R1350. The last-mentioned relay, upon operating, prepares, at RA1351, a circuit for energizing the relay R1304 and prepares, at RA1352, a point in the above-mentioned circuit for energizing the busy test relay R1320. At RA1353, the relay R1350 completes a circuit for energizing the lower winding of the switching through relay R1200, this circuit extending from ground at RA1341 by way of the off-normal springs 1216, C1274, RA1353', C1273 and the lower winding of R1200 to battery. When its lower winding is energized over this circuit, the relay R1200 partially operates to complete, at the "X" contacts associated with RA1202, a path for short-circuiting its upper winding, which path may be traced as extending from ground at RA1241 by way of RA1202, the upper

winding of R1200, C1273, RA1353', C1274 and the off-normal springs 1216 back to ground at RA1241.

During each impulse of the second digit dialed at the operator's position, the rotary magnet 1356 is energized and deenergized and operates to drive the wipers 1371 to 1374, inclusive, over the contacts of the selected level so that, at the conclusion of the digit, the enumerated wipers are left standing in engagement with the contacts terminating the conductors of the first trunk line in the selected group. Due to its slow-to-release characteristic the relay R1335, together with the two relays R1340 and R1350, is held operated until the digit is ended.

In order to adapt the incoming connector switch of Figs. 12 and 13 for automatic trunk hunting, the respective test conductors of each of the trunk lines of a trunk group, with the exception of the test conductor of the last trunk line, are connected to both the test and extra control contacts of the contact sets terminating the respective trunk lines. Thus, the control conductor C1379 of the trunk line 32 is connected to both the test and the extra control contacts embodied in the set of contacts terminating the conductors of this trunk line. When this line is made busy, ground potential is impressed upon the control conductor C1379, whereas, an idle condition of the line is indicated by the absence of any potential thereon. Assuming that the trunk line 32 is the third line of the selected group and that the first two trunk lines of the group are busy, when the wipers 1371 to 1374, inclusive, are driven into engagement with the contacts of the contact set terminating the first line, the above-mentioned circuit is completed for energizing the relay R1304, this circuit extending by way of the grounded test conductor of the selected line, the wiper 1374, RA1364, RA1351, RA1306 and the winding of R1304 to battery. When energized over this circuit, the relay R1304 operates to complete, at RA1307, a holding circuit for itself, which holding circuit extends from ground by way of RA1242, C1271, RA1307 and the winding of R1304 to battery.

At the end of the second digit, the line relay R1235 is held operated and the continued de-energization of R1335 causes the latter relay to restore. Upon restoring, the relay R1335 opens, at RA1337, the holding circuit for R1340. At RA1336, the relay R1335 completes the above-mentioned circuit for energizing the lower winding of the busy test relay R1320, which circuit may be traced as extending from ground on the control conductor of the first trunk line of the selected group, by way of the wiper 1373, RA1352, RA1353, RA1336 and the lower winding of R1320 to battery. When its lower winding is energized over this circuit, the relay R1330 operates to complete, at RA1325, an obvious path for short-circuiting the lower winding of R1340, thereby to enhance the slow-to-release characteristic of the last-mentioned relay. At RA1326, the relay R1320 opens a point in the previously traced pulsing circuit by way of which the rotary magnet 1356 and the relay R1335 were energized during the impulses of the second digit. At RA1327 the relay R1320 shunts the armature RA1353' of the operated relay R1350, thereby to complete a multiple path short-circuiting the upper winding of R1200. At RA1329, the relay R1320 prepares a circuit for impressing busy tone voltage upon the calling loop circuit. At RA1323, the relay R1320 prepares a holding circuit for

itself. At RA1324, the relay R1320 completes a circuit for energizing the relay R1330, this circuit extending by way of the grounded control conductor of the selected trunk line, the wiper 1374, RA1364, RA1351, RA1324, the armature 1257 and the winding of R1330 to battery. The relay R1330 now operates to complete, at RA1332, a holding circuit for the relay R1340, this holding circuit extending from ground at RA1242 by way of C1271, RA1332, RA1337 and the upper winding of R1340 to battery. At RA1331, the relay R1330 completes a holding circuit for itself, which holding circuit may be traced as extending from ground, at RA1241, by way of C1265, RA1331, RA1324, the armature 1257 and the winding of R1330 to battery. At RA1332, the relay R1330 completes an alternative circuit for energizing the rotary magnet 1356, this circuit extending from ground at RA1242 by way of C1271, RA1332, RA1366 and the winding of the magnet 1356 to battery. When energized over this alternative circuit, the magnet 1356 operates to step the wipers of the mechanism 1370 one step or into engagement with the contacts terminating the second trunk line of the selected group. At its armature 1257, the magnet 1356 also opens a point in the common portion of the operating and holding circuits for R1330, causing this relay to restore. Upon restoring, the relay R1330 opens, at RA1332, the operating circuit for the magnet 1356, whereupon this magnet is deenergized and the armature 1257 is restored to reprepare the operating circuit for R1330. Since the second trunk line of the selected group is also assumed to be busy, the relay R1330 is energized from ground on the control conductor of the second trunk line immediately the armature 1257 of the rotary magnet 1356 is restored. Hence, R1330 is caused to reoperate to again complete, at RA1332, the alternative operating circuit for the rotary magnet 1356, causing this magnet to step the wipers of the switching mechanism 1370 a second step or into engagement with the contacts terminating the conductors of the trunk line 32. Since the trunk line 32 is assumed to be idle, no further operation of the rotary magnet 1356 occurs. It is pointed out, however, that the interrelated operation of this magnet and the relay R1330 continues until an idle trunk line of the selected group is found or until all of the trunk lines have been tested and found busy. If all of the trunk lines of the selected group are busy, the interrelated operation of the relay R1330 and the magnet 1356 is arrested when the wipers of the mechanism 1370 are stepped into engagement with the contacts terminating the conductors of the last trunk line in the group. This is by virtue of the arrangement whereby the test conductor of the last trunk line in the group is not connected to the extra control contact of the contact set terminating the last trunk line. Hence, no circuit is available for causing the reoperation of the relay R1330 when the last trunk line is selected.

Since the relay R1330 does not reoperate when the wipers of the switching mechanism 1370 are operated into engagement with the contacts terminating the conductors of the last trunk line of a selected group at a time when all of the trunk lines of the group are busy, the relay R1340 restores after an interval to open the operating circuit for the relay R1350. Upon restoring, the last-mentioned relay completes the above-mentioned holding circuit for the busy test relay R1320, this circuit extending from ground at

RA1241 by way of RA1212, C1268, RA1313, RA1323, RC1354, RA1353, RA1336 and the lower winding of R1320 to battery. At RA1354, the relay R1350 completes the above-mentioned circuit for impressing busy tone voltage upon the calling loop circuit, thereby to signal the operator that the desired connection cannot be obtained. The circuit traversed by the busy tone current may be traced as extending from one terminal of the busy tone source, not shown, by way of the condenser 1254, RA1368, RA1354', RA1329, C1279, RA1215, the condenser 1229, RA1208, C854, the springs 821 and 822, RA1785, RC1786, the winding 776, the condenser 778, the winding 775, RC1783, RA1782, the springs 817 and 816, C853, RA1201, the condenser 1228, RA1211, the winding of the line balancing impedance element 1219 and the exchange battery to the opposite terminal of the busy tone source. The alternating character of the current traversing the repeating transformer windings 775 and 776 causes a corresponding induced voltage to be developed in the windings 772 and 773 so that the receiver 501 is energized and the usual busy tone signal is reproduced. Following the receipt of busy tone, the operator may inform the calling subscriber that the desired connection cannot immediately be obtained, and initiate the release of the connector switch illustrated in Figs. 12 and 13 in the manner described hereinafter.

In the present case, it is assumed that the trunk line 32 is the first available idle trunk line of the selected group. When, therefore, the wipers of the switching mechanism 1370 are operated into engagement with the bank contacts terminating the conductors of this trunk line, no further circuit is available for energizing the relay R1330 and, hence, the interrelated operation of this relay and the rotary magnet 1356 is arrested. Also, the absence of ground potential upon the control conductor C1379 results in the deenergization and restoration of the busy test relay R1320. With the relay R1330 restored, the holding circuit for the relay R1340 is held open so that this relay and the relay R1350 restore in the order named. When the relay R1350 restores, it interrupts, at RA1353', a point in the previously traced path short-circuiting the upper winding of R1200, permitting the two windings of the relay R1200 to be energized in series over a circuit extending from ground by way of RA1241, RA1292 and the two series connected windings of R1200 to battery. The relay R1200 now completes its operation and, in so doing, switches the calling loop circuit through to the trunk line 32 to cause the seizure of the repeater illustrated in Figs. 17 and 18. Also, the relay R1200, upon operating, opens, at RA1205, a point in the circuit, traced herein-after, for energizing the release magnet 1208. At RA1204, the relay R1200 opens a point in the pulsing circuit, traced previously, for energizing the relay R1335 in series with the rotary magnet 1356. At RA1203, the relay R1200 prepares a multiple holding circuit for itself, which circuit is traced herein-after and completed in response to the operation of the line and hold relays embodied in the seized repeater shown in Figs. 17 and 18. At RA1201 and RA1206 and their respective associated resting contacts, the relay R1200 opens two points in the previously traced circuit over which the line relay R1235 is being held energized, causing this relay to restore to open, at RA1236, the operating circuit for the hold relay R1240. The last-

mentioned relay, upon restoring, opens, at RA1241, a point in the original holding circuit for R1200. At RA1244, the relay R1240 prepares a point in the above-mentioned circuit for energizing the release magnet 1208. At RA1242, the relay R1240 opens a point in the holding circuit for R1304 causing the last-named relay to

When the calling loop circuit is switched through to the repeater illustrated in Figs. 17 and 18, the line relay R1705 and the hold relay R1700 are caused to operate to complete the previously mentioned alternative holding circuit for the switching-through relay R1200 before the hold relay R1240 of the operated incoming connector switch restores in the manner just explained. More particularly, the line relay R1705 is energized in response to the operation of R1200 over a circuit which may be traced as extending from ground at the upper terminal of the lower winding of R1705 by way of the lower winding of R1705, the lower winding of R1710, RA1715, C1380, the wiper 1372, C1278, RA1206, C854, the springs 821 and 822, RA185, RC1786, the winding 776, the resistor 797', the upper winding of R1790, RA1797, the winding 775, RC1783, RA1782, the springs 817 and 816, C853, RA1201, C1262, the wiper 1371, C1378, RA1714, the upper winding of R1710 and the upper winding of R1705 to battery. Upon operating, the relay R1705 completes, at RA1706 and its associated working contact, on obvious circuit for energizing the slow-acting hold relay R1700. The relay R1700, upon operating, completes, at RA1701, an obvious path for applying ground potential to the control conductor C1379, thereby to mark the trunk line 32 as busy in the bank contacts of the connector switches to which this line extends. When the conductor C1379 is connected to ground, the above-mentioned multiple holding circuit for R1200 is completed, which circuit may be traced as extending by way of C1379, the wiper 1373, C1266, RA1203, RA1202 and the two series connected windings of R1200 to battery.

The relay R1700, upon operating, prepares, at RA1703, a circuit traced herein-after for energizing the relay R1730. At RA1702, the relay R1700 completes a circuit for energizing the slow-acting relay R1800, this circuit extending from ground by way of RA1702, RA1736, C1783, RA1812 and the winding of R1800 to battery. When the relay R1800 operates, it prepares, at RA1801, a holding circuit for the relay R1830; completes, at RA1802, a circuit extending from ground at RA1832 for energizing the relay R1840; completes, at RA1803, a circuit extending from ground at RA1833 for energizing the slow-acting relay R1820; and prepares, at RA1804, a circuit, traced herein-after, for energizing the slow-to-operate relay R1805. The slow-acting relay R1820, upon operating, disconnects, at its armatures RA1821 and RA1822, the line conductors C1885 and C1886 of the trunk line 31 from the respective line terminals of the repeating transformer windings 1878 and 1879. The relay R1840, upon operating, connects, at its armatures RA1841 and RA1843, the trunk line conductors C1885 and C1886 to opposite terminals of the alternating current source, not shown but provided in the exchange B. At RA1842, the relay R1840 completes the above-mentioned circuit for energizing the slow-to-operate relay R1805. After a time interval, the last-mentioned relay operates to prepare, at RA1806, a multiple holding circuit for R1830 and to complete, at RA1807, an obvious circuit

for energizing the relay R1810. At RA1809, the relay R1805 completes the above-mentioned circuit for energizing the relay R1730, this circuit extending from ground by way of RA1809, C1795, RA1703, the winding of R1730 and the resistor 1731' to battery. The relay R1810, upon operating, prepares, at RA1811, a point in the operating circuit, traced hereinafter, for the operating magnet 1772 of the minor switch 1770. At RA1812, the relay R1810 opens a point in the above-traced operating circuit for R1800. Substantially simultaneous with the operation of R1810, the relay R1730 operates to open, at RA1736, a further point in the operating circuit for R1800. At RA1734, RA1735 and RA1737, the relay R1730, upon operating, prepares operating circuits, traced hereinafter, for energizing the relays R1830, R1840 and R1820, respectively. At RA1737', the relay R1730 prepares an operating circuit, traced hereinafter, for the relay R1712. At RA1732, the relay R1730 prepares an alternative path, described hereinafter, for maintaining ground potential upon the control conductor C1379 on the trunk line 32. At RA1738, the relay R1730 completes a holding circuit for itself, which holding circuit extends from ground at RA1757 by way of RA1738, the winding of R1730 and the resistor 1731' to battery. At its two armatures RA1731 and RA1739, the relay R1730 connects the line conductors C1378 and C1380 of the trunk line 32 to the line terminals of the two repeating transformer windings 1874 and 1875.

When the operating circuit for the relay R1800 is interrupted in response to the operation of the relays R1730 and R1810 in the manner pointed out above, it restores to open, at RA1802, RA1803 and RA1804, respectively, the respective operating circuits, described above, for the relays R1840, R1820 and R1805, causing all of these relays to restore. When the two relays R1840 and R1820 restore, the trunk line conductors C1885 and C1886 of the trunk line 37 are disconnected from the alternating current source provided in the exchange C and are reconnected to the line terminals of the repeating transformer windings 1878 and 1879. The relay R1805, upon restoring, opens, at RA1809, a point in the above-traced operating circuit for the relay R1730 and opens, at RA1807, the operating circuit for R1810, causing the last-mentioned relay to restore. Following the restoration of the relays R1810 and R1820, the repeater illustrated in Figs. 17 and 18 is conditioned to respond to the impulses of the line selecting digits dialed at the operator's position in the exchange B and to repeat these impulses by way of the trunk line 37 to the repeater located in the exchange C, and terminating the distant end of the trunk line, this latter repeater being illustrated in Figs. 26 and 27.

When the seizing pulse of alternating voltage is impressed upon the conductors of the trunk line 37 in the manner just explained, the alternating current relay R2650 is energized over a circuit which may be traced as extending from one side of the ringing current source by way of RA1841, C1885, RA2631, RA2646, the winding 2616, the condenser 2616', the winding of R2650, the winding 2617, RA2647, C1886 and RA1843 to the opposite side of the ringing current source. When energized over this circuit, the alternating current relay R2650 operates to complete, at RA2652, a circuit for energizing the upper winding of R2710, this circuit extending

from ground by way of RA2652, C2689, RA2738, RA2716 and the upper winding of R2710 to battery. When its upper winding is energized over this circuit, the relay R2710 partially operates to complete, at the "X" contacts associated with RA2714, a path for short-circuiting its lower winding, this path extending from ground by way of RA2714, RC2723, RA2722, the lower winding of R2710, RA2716, RA2738 and C2689 back to ground at RA2652. At the end of the seizing pulse, when the relay R1840 restores to disconnect the conductors of the trunk line 37 from the alternating current source provided in the exchange B, the alternating current relay R2650 is deenergized and restores to open, at RA2652, a point in the path short-circuiting the lower winding of R2710. The two windings of the last-mentioned relay are now energized in series over a circuit extending from ground by way of RA2714, RC2723, RA2722 and the two series connected windings of R2710 to battery. When its two windings are energized in series, the relay R2710 completes its operation to open, at RA2716, a point in the above-traced circuit for energizing its upper winding and to complete, at RA2712, a path extending by way of RA2781 for applying ground to the control conductor C2895, thereby to mark the repeater illustrated in Figs. 26 and 27 as busy in the bank contacts of the switching selector repeaters having access thereto. At RA2711, RA2715 and RA2719, the relay R2710 completes a loop circuit extending to the incoming connector switch illustrated in Figs. 31 and 32, thereby to seize the last-mentioned switch. At RA2713, the relay R2710, upon operating, prepares a path, traced hereinafter, for short-circuiting the winding of R2730 during operation of the minor switch 2785. At RA2718, the relay R2710 completes a circuit for energizing the slow-to-release relay R2605, this circuit extending from ground by way of RA2718, C2694, RA2601, RA2621 and the winding of R2605 to battery. When energized over this circuit, the relay R2605 operates to prepare, at RA2607, a holding circuit for itself and to open, at RA2608, a point in one circuit for energizing the relay R2640. At RA2606, the relay R2605 prepares a circuit, traced hereinafter, for energizing the relay R2620.

The relay R2710, upon operating, also completes a circuit for energizing the upper winding of R2700 and the lower winding of R2640 in parallel, one branch of this circuit extending from ground at RA2711 by way of the upper winding of R2700 to battery, and the other branch of this circuit extending from ground at RA2711 by way of C2691, RA2624 and the lower winding of R2640 to battery. At this time, the lower winding of R2700 is differentially energized with respect to the upper winding of R2700 over the loop circuit extending to the seized incoming connector switch illustrated in Figs. 31 and 32 and, thus, the relay R2700 does not operate. The relay R2640, however, operates to open, at RA2642, a point in the circuit, traced hereinafter, for energizing the relay R2630 and to open, at RA2641, a point in the circuit, traced hereinafter, for energizing the release magnet 2788 of the minor switch 2785. At RA2643, the relay R2640 opens a point in the operating circuit for the slow-acting relay R2645 and prepares a point in the operating circuit for the slow-to-operate relay R2660. At RA2641 and its associated working contact, the relay R2640 prepares a holding circuit for itself and a circuit, traced hereinafter,

for energizing the operating magnet 2787 of the minor switch 2785. At RA2642 and its associated working contact, the relay R2640 completes a circuit extending by way of RA2657 for energizing the slow-acting relay R2670, thereby to initiate the cyclic operation of the three relays R2670, R2660 and R2655 which respectively correspond to the relays R1100, R1105 and R1110 embodied in the repeater illustrated in Figs. 10 and 11. More particularly, when the relay R2670 operates, it completes, at RA2674, the above-mentioned operating circuit for R2660, which circuit extends from ground at RA2643 by way of RA2674 and the winding of R2660 to battery. The relay R2660, upon operating, completes, at RA2662, the operating circuit for R2655, which latter relay, upon operating, opens, at RA2657, the operating circuit for R2670. The relay R2670, upon restoring, causes the sequential restoration of R2660 and R2655, the last-mentioned of which, upon falling back, recompletes the operating circuit for R2670. During each cycle of operation of the three relays noted and when R2655 operates, the above-mentioned circuit is completed for energizing the operating magnet 2787 of the minor switch 2785, this circuit extending from ground at RA2641 by way of RA2656, C2678 and the winding of the magnet 2787 to battery. Each time the magnet 2787 is energized, it cooperates with its associated ratchet and pawl mechanism, not shown, to step the wiper 2786 of the minor switch 2785 one step in a clockwise direction so that this wiper is successively moved into engagement with succeeding contacts of the contact field embodied in the minor switch. The purpose of the arrangement just described is to cause the forced release of the partially operated switch train in the event the dialing operation at the calling station is not started within a predetermined time interval. The manner in which this release operation is performed is explained in a succeeding portion of the specification. It is pointed out here, however, that the forced release of the partially completed connection is not initiated until the wiper 2786 of the switch 2785 is operated to its ninth off-normal position, and the time interval required for operation of this wiper to the position noted is amply sufficient to permit the calling party to start the dialing operation.

As pointed out above, when the relay R2710 operates, a loop circuit is completed by way of the trunk line 61 to the incoming connector switch illustrated in Figs. 31 and 32, thereby to cause the seizure of this connector switch. More particularly, when R2710 operates, the line relay R3125 embodied in the incoming connector switch is energized over a circuit which may be traced as extending from ground at the lower terminal of the lower winding of R3125 by way of this winding, the lower winding of R3120, RC3116, RA3115, RA3105, C2891, RA2719, C2695, the winding 2619, C2684, the resistor 2701', the lower winding of R2700, RA2715, C2686, RA2613, the winding 2618, C2675, RA2711, C2890, RA3102, RA3112, RC3113, the upper winding of R3120 and the upper winding of R3125 to battery. It will be noted that the two windings of R3120 are energized over the circuit just traced. Since these windings are differentially connected, however, the relay R3120 does not operate at this time. The line relay R3125, however, operates when energized over the loop circuit as traced above and completes, at RA3126, a circuit extending from ground at RA3103 for energizing

the slow-acting hold relay R3130. The relay R3130, upon operating, completes, at RA3131, a path extending from ground at RA3236 and by way of C3171 for applying ground potential upon the ringing and tone apparatus start conductor C3131', thereby to initiate the operation of the ringing and tone apparatus provided in the exchange C in the usual manner. At RA3132 the relay R3130 completes an obvious circuit for energizing the slave relay R3140. When the relay R3140 operates it prepares, at RA3141, a point in the common portion of the holding circuits, traced hereinafter, for the relays R3150, R3235 and R3240. At RA3143, the relay R3140 prepares a circuit for energizing the slow-acting relay R3160 in parallel with the lower winding of R3170 and the operating magnet 3257 of the rotary switch 3250. At RA3142, the relay R3140 prepares a further point in the circuit for energizing the operating magnet 3257 of the line selecting rotary switch 3250. Following the operation of the relay R3140, the incoming connector switch illustrated in Figs. 31 and 32 is conditioned to respond to the impulses of the third line selecting digit dialed at the operator's position in the exchange B.

During operation of the calling device 508 to transmit the impulses of the third digit, the relay R780 operates, in the manner explained previously, to include the impulsing springs 510 of the calling device in the loop circuit which is now switched through to the repeater illustrated in Figs. 17 and 18. During the back stroke of the dial embodied in the calling device 508, the impulsing springs are opened a number of times determined by the number of impulses in the digit. Each time these springs are opened the loop circuit extending to the last-mentioned repeater is interrupted and, thus, the line relay R1705 is caused to follow the dial impulses. More particularly, the line relay R1705 restores during the open circuit period of each impulse to complete, at RA1707, an alternative circuit for energizing the slow-acting relay R1820, this circuit extending from ground by way of RA1707, RA1731, C1784 and the winding of R1820 to battery. The relay R1820 operates at the beginning of the first impulse and, due to its slow-to-release characteristic, remains operated until shortly after the digit is ended. This relay, upon operating, disconnects, at its armatures RA1821 and RA1822, the line conductors C1885 and C1886 of the trunk line 37 from the line terminals of the repeating transformer windings 1878 and 1879. At RA1706 and its associated working contact, the relay R1705, upon restoring, opens the operating circuit for the hold relay R1700, but the last-mentioned relay, due to its slow-to-release characteristic, remains operated during impulsing. At RA1706 and its associated resting contact, the relay R1705 completes an alternative circuit for energizing the relay R1840, which circuit may be traced as extending from ground by way of RA1706, RA1735, C1731 and the winding of R1840 to battery. Upon operating, the relay R1840 connects, at its armatures RA1841 and RA1843, the line conductors C1885 and C1886 of the trunk line 37 to the opposite terminals of the alternating current source provided in the exchange B. Obviously, at the end of the open circuit period of each impulse, when the line relay R1705 reoperates, the above-traced operating circuit for the pulsing relay R1840 is interrupted, causing the last-mentioned relay to restore to disconnect the conductors of the trunk line 37 from

the alternating current source. Thus, the line relay R1705 and the pulsing relay R1840 co-operate to cause the dialed impulses of the third and succeeding digits dialed at the operator's position to be repeated as alternating current impulses over the trunk line 37 to the repeater illustrated in Figs. 26 and 27 and located in the exchange C. As explained above, at the end of each digit and when the shunt springs 509 of the calling device 508 provided at the operator's position are opened, the slow-acting relay R540 restores to open the previously traced operating circuit for R780, which latter relay, upon restoring, reconnects the outgoing line terminals of the repeating transformer 771 to the line conductors of the link line 832. Also, at the end of each digit, the line relay R1705 embodied in the repeater illustrated in Figs. 17 and 18 remains operated to hold interrupted the operating circuits for R1820 and R1840, causing the two last-mentioned relays to restore so that the line conductors of the trunk line 37 are disconnected from the alternating current source provided in the exchange B and are reconnected to the outgoing line terminals of the repeating transformer 1873.

The alternating current relay R2650 responds to the alternating current impulses transmitted by way of the trunk line 37 to the repeater illustrated in Figs. 26 and 27 and causes the impulses to be repeated to the incoming connector switch illustrated in Figs. 31 and 32. More particularly, during the open circuit period of the first impulse when the first pulse of alternating current is projected over the trunk line 37, the relay R2650 operates to complete, at RA2652, a circuit for energizing the lower winding of the relay R2600 in parallel with the winding of the slow-acting relay R2705. This circuit extends from ground by way of RA2652, C2689, RA2738, RA2716 and C2688 to RA2614 where it divides, one branch extending through the lower winding of R2600 to battery, and the second branch extending by way of C2687 and the winding of R2705 to battery. The relay R2705 now operates and, due to its slow-to-release characteristic, remains operated throughout the series of impulses. At RA2707, the relay R2705 completes a path, including the conductor C2681 and the line conductor C2675, for short-circuiting the repeating transformer winding 2618. Similarly, at RA2708, the relay R2705 completes a path including the conductor C2685 for shunting the series path including the transformer winding 2619, the resistor 2701 and the lower winding of R2700. By completing the two short-circuiting paths just described, the slow-acting relay R2705 clears the loop circuit extending to the incoming connector switch illustrated in Figs. 31 and 32 of all unnecessary impedances and provides a low resistance pulsing circuit.

When its lower winding is energized over the circuit just traced, the relay R2600 operates to prepare, at RA2603, a circuit for energizing its upper winding and to complete, at RA2602, a path for short-circuiting the lower winding of R2610, which path may be traced as extending from ground at RA2718, by way of C2694, RA2602, the lower winding of R2600, RA2614, C2688, RA2716, RA2738 and C2689 back to ground at RA2652. At RA2601, the relay R2600 opens a point in the previously traced operating circuit for R2605 and completes a circuit for energizing the relay R2620, this latter circuit extending from ground at RA2718 by way of C2694, RA2601,

RA2606 and the winding of R2620 to battery. Upon operating, the relay R2620 completes, at RA2622, a holding circuit for itself, which circuit extends from ground at RA2718 by way of C2694, RA2622 and the winding of R2620 to battery. At RA2621, the relay R2620 opens a further point in the previously traced operating circuit for the relay R2605. At RA2623, the relay R2620 prepares a further point in the holding circuit for the relay R2605. At RA2624, the relay R2620 interrupts the previously traced operating circuit for R2640, permitting the last-named relay to restore at the end of the cycle of operation of the three relays R2655, R2660 and R2670 which is in progress at the time the relay R2620 operates. When the relay R2640 restores, it opens, at RA2642 and RA2643, respectively, points in the respective operating circuits for the relays R2670 and R2660. At RA2641 and its associated working contact, the relay R2640 opens a further point in its own holding circuit and opens a point in the circuit for energizing the operating magnet 2787 of the minor switch 2785. At RA2641 and its associated resting contact, the relay R2640, upon restoring, completes a circuit for energizing the release magnet 2788 of the minor switch 2785, which circuit may be traced as extending from ground by way of RA2641, C2683, the off-normal springs 2789 and the winding of the magnet 2788 to battery. The resulting operation of the release magnet 2788 causes the wiper 2786 to be restored to its home position in the usual manner, at which time the springs 2789 are opened to interrupt the operating circuit for the release magnet. From the foregoing description it will be apparent that, if the first impulse of the third series of impulses dialed at the operator's position in the exchange B is transmitted to the repeater illustrated in Figs. 26 and 27, before the wiper 2786 is driven to its off-normal position, the operation of the minor switch 2785 is arrested to prevent the partially established connection from being forcibly released.

At the end of the open circuit period of the first impulse dialed at the operator's position in the exchange B, the alternating current source provided in this exchange is disconnected from the conductors of the trunk line 37 and the alternating current relay R2650 restores to complete the above-mentioned holding circuit for the relay R2605, this circuit extending from ground at RA2652 by way of RA2623, RA2607 and the winding of R2605 to battery. Due to its slow-to-release characteristic the relay R2605 remains operated during operation of the relay R2650 to follow the alternating current pulses transmitted thereto. At RA2652 and its associated working contact, the relay R2650 opens a point in the operating circuit for R2600 and interrupts the above-traced path short-circuiting the lower winding of R2610. The lower winding of the relay R2610 is now energized in series with the lower winding of R2600 over a circuit which may be traced as extending from ground at RA2718 by way of C2694, RA2602, the lower winding of R2610 and the lower winding of R2600 to battery. When its lower winding is energized over the circuit just traced, the relay R2610 operates to open, at RA2614, a further point in the above-traced operating circuit for the two relays R2600 and R2705 and to complete, at RA2612, an obvious path for short-circuiting its upper winding, thereby to render itself slow to release. At RA2613, the relay R2610, upon operating, opens a point in the loop circuit extending to the in-

coming connector switch illustrated in Figs. 31 and 32. Thus, the open circuit period of the first impulse is repeated by the relay R2610 to the seized incoming connector switch. At RA2611, the relay R2610 completes the above-mentioned and obvious circuit for energizing the upper winding of R2600. The two windings of R2600 are differentially wound so that, when the upper winding thereof is energized over the circuit just described, the relay R2600 restores to open, at RA2602, a point in the circuit traced above for energizing the lower winding of R2610 in series with the winding of R2600. At RA2603, the relay R2600, upon restoring, opens a point in the circuit for energizing its upper winding. At RA2604, the relay R2600 opens a point in the previously traced operating circuit for R2620 and prepares a point in the previously traced operating circuit for the slow-to-release relay R2605. A short time interval after the interruption of its operating circuit, the relay R2610 restores to recomplete, at RA2613, the loop circuit extending to the incoming connector switch illustrated in Figs. 31 and 32. At RA2614, the relay R2610 reprepares the operating circuit for the two relays R2600 and R2705. At RA2611, the relay R2610 opens a further point in the circuit described above for energizing the upper winding of R2600 and, at RA2612, it opens a point in the path short-circuiting its upper winding.

During each succeeding impulse the three relays R2650, R2600 and R2610 interact in the manner just described to cause the impulse to be repeated to the succeeding incoming connector switch. Thus, at the beginning of the open circuit period of the second impulse, the alternating current relay R2650 is again energized and operates to complete the previously traced operating circuit for the two relays R2600 and R2705. The relay R2600, upon operating, short-circuits the lower winding of R2610 and, in so doing, prepares the circuit for energizing its own lower winding in series with the lower winding of R2610. At the end of the open circuit period of the second impulse, when the relay R2650 again restores, the short circuit is removed from the lower winding of R2610 and the last-mentioned relay operates to again open the loop circuit extending to the succeeding incoming connector switch. Also, the relay R2610 recompletes the circuit for energizing the upper winding of R2600, causing the relay R2600 to restore and open the operating circuit for R2610. After an interval determined by the slow-to-release characteristic of R2610, this relay again restores to recomplete the loop circuit extending to the succeeding incoming connector switch. It will be noted that the duration of the open circuit period of each impulse transmitted through operation of R2610 to the tandem-connected incoming connector switch of Figs. 31 and 32 is, within limits, independent of the period of the corresponding alternating current pulse transmitted by way of the trunk line 31 to the repeater shown in Figs. 26 and 27. Thus, when once operated, the extent of the period during which R2610 remains operated is determined primarily by the slow-to-release characteristic of this relay rather than by the period during which R2650 is restored.

Although the operation of the impulse repeating relays embodied in the repeater illustrated in Figs. 26 and 27 has been described with reference to the impulses of the first digit, it will be understood that this relay equipment operates in exactly the same manner during the impulses of ad-

ditional digits dialed at the operator's position and transmitted to this repeater. At the end of each digit, the relay R2650 remains in its restored position to hold the previously traced holding circuit for R2605 completed. With the relay R2650 in its restored position, the operating circuit for R2705 is held open at the restored armature RA2652. Hence, the relay R2705 is caused to restore shortly following the end of each digit to open, at RA2707 and RA2708, the two short-circuiting paths traced previously, namely, the path for short-circuiting the transformer winding 2618 and the path for short-circuiting the transformer winding 2619 in series with the resistor 2701 and the lower winding of R2700.

The incoming connector switch illustrated in Figs. 31 and 32 responds to the impulses repeated thereto by way of the repeater shown in Figs. 26 and 27 by selecting the desired line. In this regard it is pointed out that the incoming connector switch of Figs. 31 and 32 is arranged to provide switching-through service on trunk calls routed by way of this switch and also for different modes of operation, depending upon whether a called subscriber's line is of the multiplex type or of the single party or duplex type. In the illustrated arrangement, the first set of contacts in the bank contact field of the rotary switch 3250 is utilized to terminate the trunk line 64 extending to the repeater 57 by way of which connections are routed to the switching equipment provided in the exchange D and the remaining contact sets are divided into three groups for terminating three different groups of lines. The second contact set of the bank contact field embodied in the rotary switch 3250 is reserved as a preliminary or starting position for the selection of subscribers' lines in the first group of lines. The lines of this first group are terminated at the contact sets numbered from 3 to 8, inclusive, of the rotary switch contact field and the ninth set of contacts is reserved as the preliminary or starting position for the selection of lines in the second group. The lines of this second group are terminated at the contact sets numbered from 10 to 19, inclusive, in the rotary switch contact field. The twentieth contact set of the contact field is reserved as the preliminary or starting position for the selection of the subscribers' lines forming the third group accessible to the incoming connector switch. The lines of this third group are terminated at the contacts forming the contact sets numbered from 21 to 25, inclusive, of the contact field, and the twenty-fifth contact set represents the home position of the switch. With the bank contact wiring arrangement just described, it will be apparent that, to select the trunk line 64 extending to the repeater 57, it is only necessary to transmit to the incoming connector switch a single impulse in order that the desired line shall be selected. In order to select a subscriber's line in the first group, a first series of two impulses followed by a second series of from one to six impulses, depending upon the line being called, must be transmitted to the incoming connector switch. If the desired line is in the second group of subscribers' lines, a first series of three to nine impulses followed by a second series of from one to ten impulses must be transmitted to the incoming connector switch for the purpose of causing the wipers of the rotary switch 3250 to be operated into engagement with the contacts terminating the desired line. In order to select a line in the third group of lines, a first series of ten impulses followed by a second series of from

one to five impulses, depending upon the line being called, are required to cause the desired line selection to be performed on the part of the incoming connector switch. In the present case, if it be assumed that the substation T_5 associated with the line **60** is the substation desired by the calling party at the substation T_1 , and further that the line **60** is the third line in the first group of subscribers' lines, the third and fourth digits dialed at the operator's position in the exchange **B** will necessarily comprise two and three impulses, respectively. During the open circuit period of each impulse transmitted to the incoming connector switch, the line relay **R3125** restores to complete the previously mentioned circuit for energizing the relay **R3160** in parallel with the lower winding of **R3170** and the operating magnet **3257** of the rotary switch **3250**. This circuit extends from ground at **RA3103** by way of **RA3126**, **RA3143**, **C3190** and **RA3203** to **C3189** where it divides, one branch extending through the winding of **R3160** to battery, a second branch extending through the lower winding of **R3170** to battery, and a third branch extending by way of **RA3142**, **RA3127**, **C3192**, **RA3246** and the winding of the magnet **3257** to battery. At the end of the open circuit period of each impulse when the line relay **R3125** reoperates, the circuit just traced is interrupted at **RA3126**. At the beginning of the first series of impulses, the relay **R3160** operates and, due to its slow-to-release characteristic, remains operated until the impulse series is ended. Upon operating, the relay **R3160** completes, at **RA3161**, an obvious circuit for energizing the slow-to-release relay **R3165** in parallel with the upper winding of **R3170**. At **RA3162**, the relay **R3160** completes a multiple circuit for maintaining the relays **R3160** and **R3170** operated during the first series of impulses transmitted to the incoming connector switch and for transmitting the impulses to the operating magnet **3257** of the rotary switch **3250**. The relay **R3165**, upon operating, prepares, at **RA3166** and **RA3167**, an operating circuit traced hereinafter for the busy test relay **R3200**. At **RA3171** and **RC3172**, the relay **R3170**, upon operating, applies ground potential to the test conductor **C3195** and, in so doing, completes a circuit for energizing the lower winding of **R3150** in series with the winding of **R3155**. This circuit extends from ground at **RA3141** by way of **C3179**, **RA3244**, **C3187**, **RA3172**, **RA3171**, **C3195**, the test wiper **3255**, the twenty-fifth contact of the set **3276**, **C3197**, **RA3158**, the lower winding of **R3150** and the winding of **R3155** to battery. Upon operating, the relay **R3155** completes a holding circuit for itself and then interrupts, at **RA3158** and its associated resting contact, its own operating circuit as traced above. The holding circuit for **R3155** may be traced as extending from ground at **RA3141** by way of **C3179**, **RA3244**, **C3187**, **RA3172**, **RA3171**, **RA3159**, **RA3158**, the lower winding of **R3150** and the winding of **R3155** to battery. At **RA3156**, the relay **R3155** opens a point in the circuit, traced hereinafter, for energizing the slow-to-operate line switching relay **R3240**. At **RA3157**, the relay **R3155** prepares a second circuit, traced hereinafter, for energizing the operating magnet **3257** of the rotary switch **3250**. When its lower winding is energized in series with the winding of **R3155**, the relay **R3150** partially operates to complete, at the "X" contacts associated with **RA3152**, a circuit extending from ground at **RA3141** for energizing its upper winding. When its upper winding is energized, the relay **R3150** completes its

operation to prepare, at **RA3151**, a point in the above-mentioned circuit for energizing the line switching relay **R3240**.

At the end of the open circuit period of each impulse transmitted to the incoming connector switch of Figs. 31 and 32, the line relay **R3125** is caused to reoperate to open the above-traced circuit for energizing the operating magnet **3257** of the rotary switch **3250**. As a consequence, the ratchet and pawl mechanism associated with this magnet operates to advance the wipers **3251** to **3256**, inclusive, one step during the closed circuit period of each impulse. Hence, at the conclusion of the first series of two impulses transmitted to the incoming connector switch illustrated in Figs. 31 and 32, the enumerated wipers are left standing in engagement with their respective associated second contacts. During the inter-digit pause between the two series of impulses transmitted to the incoming connector switch, the line relay **R3125** remains operated to hold interrupted the above-traced circuit for energizing the winding of **R3160**, the lower winding of **R3170** and the winding of the magnet **3257** in parallel, causing the relay **R3160** to restore. Upon restoring, the relay **R3160** opens, at **RA3161**, a point in the holding circuit for **R3170** and a point in the operating circuit for **R3165**. The relay **R3170**, upon restoring, opens, at **RA3171** and **RA3172**, a point in the holding circuit for **R3155**, which latter relay now restores to reprepare, at **RA3156**, a point in the operating circuit for the line switching relay **R3240**. This circuit is further prepared at **RA3166** and its associated resting contact in response to the restoration of **R3165**.

The line relay **R3125** follows the impulses of the second series of impulses transmitted to the incoming connector switch in the exact manner described above. At the beginning of the first impulse of this second series, the three relays **R3160**, **R3165** and **R3170** are all caused to reoperate in the manner explained previously and remain operated until shortly following the end of the last impulse of the series. The relay **R3160**, upon reoperating, recompletes, at **RA3162**, the shunt around the armature **RA3203** of the busy test relay **R3200**, thereby to prevent the impulsive circuit from being interrupted in response to the operation of the relay **R3200** as the wipers of the rotary switch **3250** pass over the contacts terminating the control conductors of busy lines. At **RA3166** and **RA3167**, the relay **R3165** prepares a test circuit, traced hereinafter, for energizing the busy relay **R3200**. During the open circuit period of each impulse, the operating magnet **3257** of the rotary switch **3250** is energized over the impulsive circuit traced previously, this magnet being deenergized at the end of each open circuit period, thereby to cause the wipers of the switch **3250** to be advanced at the rate of one step for each impulse. At the end of the second series of impulses, the wipers of the switch **3250** are left standing in engagement with the contacts terminating the conductors of the desired called line. In the present assumed case wherein the called line **60** is the third line of the first group of lines and the second series of impulses transmitted to the incoming connector switch comprises three impulses, the wipers of the switch **3250** are left standing in engagement with their respective associated fifth contacts.

The relay operations which occur following the selection of the called line in the manner just described depend upon the idle or busy condition of the line. Before describing these relay opera-

tions, however, and in order to complete the description of the operation of the incoming connector switch shown in Figs. 31 and 32, the operation of this switch to select a line in each of the other two line groups will be briefly considered. If the desired called line is included in the second group of subscribers' lines the wipers 3251 to 3256, inclusive, of the switch 3250 are caused to be driven over the contacts terminating the lines of the first group during the interdigit pause between the first and second series of impulses transmitted to the switch. Thus, if the desired line is included in the second group of lines, such that the first series of impulses transmitted to the incoming connector switch is made up of three impulses, the wipers of the switch 3250 are left standing in engagement with their respective associated third contacts at the end of the first impulse series. With the wipers in this position, a multiple holding circuit is completed for maintaining the relay R3155 operated, which holding circuit may be traced as extending from ground at the third contact of the contact set 3276 by way of the test wiper 3255, C3195, RA3159, RA3158, the lower winding of R3150 and the 25 winding of R3155 to battery. With the last-mentioned relay operated and when the three relays R3160, R3165 and R3170 are caused to restore during the interdigit period in the manner explained above, the above-mentioned circuit is completed for energizing the operating magnet 3257 by way of the circuit interrupting contacts associated with the armature 3258. This circuit may be traced as extending from ground by way of the multiplied third to eighth contacts of the set 3276, the test wiper 3255, C3195, RA3171 and its associated resting contact, RA3157, C3194, the armature 3258, and the winding of the magnet 3257 to battery. Due to the circuit-interrupting action of the armature 3258, the magnet 3257 is repeatedly energized over the circuit just traced to drive the wipers of the switch 3250 until the operating circuit for the magnet 3257 is interrupted at the test wiper 3255. This occurs when the wiper 3255 is operated into engagement with the open-circuited ninth contact of the contact set 3276. When the wiper 3255 is disconnected from ground, the above-traced holding circuit for R3255 is interrupted causing this relay to restore. From the foregoing description, it will be apparent that, if a first series of three impulses is transmitted to the incoming connector switch illustrated in Figs. 31 and 32, the wipers 3251 to 3256, inclusive, will be advanced into engagement with their respective associated ninth contacts before the fourth digit is dialed at the operator's position in the exchange B. The manner in which the incoming connector switch responds to the impulses of the second series of impulses transmitted thereto is exactly the same irrespective of which line group is selected.

If the desired called line is included in the third line group, namely, the lines terminating in the bank contact field of the switch 3250 at the contact sets, numbered from 21 to 25, inclusive, the first series of impulses transmitted to the incoming connector switch will necessarily comprise ten impulses so that, during the impulses of the first series, the wipers of the switch 3250 are advanced to the tenth off-normal position. When the wiper 3255 encounters the tenth contact of the set 3276, the above-traced alternative holding circuit for the relay R3155 is completed and the circuit for energizing the magnet 3257 by way of the cir- 75

cuit interrupting contacts associated with the armature 3258 is again prepared, since the tenth to nineteenth contacts of the set 3276 are also multiplied together and connected to ground. With the wipers standing in this position, the circuit for energizing the magnet 3257 is completed in response to the restoration of the relay R3170 during the interdigit pause between the third and fourth digits dialed at the operator's position. The resulting repeated energization of the magnet 3257 causes the wipers of the switch 3250 to be advanced into engagement with their respective associated twentieth contacts, at which time the wiper 3255 is disconnected from ground to open the alternative holding circuit for R3155 and the operating circuit for the magnet 3257. Here again, the manner in which the switch responds to the impulses of the second series following the selection of the third line group is exactly the same as explained previously with reference to the selection of the line 60.

Considering now the operation of the incoming connector switch when the selected called line 60 is idle at the time the wipers of the switch 3250 are operated into engagement with the contacts terminating the conductors thereof, it is pointed out that an idle condition of the line is indicated by the presence of battery potential upon the control conductor C3482 thereof. On the other hand, when this line is busy, ground potential is impressed upon the control conductor C3482 by certain of the relays embodied in the line circuit associated with the line. Assuming that the line is idle, a circuit is completed for energizing the lower winding of the slow-to-operate line switching relay R3240 shortly following the conclusion of the second series of impulses transmitted to the incoming connector switch or the fourth digit dialed at the operator's position in the exchange B. More particularly, when the three relays R3160, R3165 and R3170 restore shortly following the last impulse of the fourth digit in the manner explained previously, the relay R3240 is energized over a circuit which may be traced as extending from ground at RA3141 by way of RA3151, C3180, RA3201, the lower winding of R3240, C3181, RA3166, RA3156, C3184, the wiper 3253, C3482, RA3422 and the winding of R3440 to battery. When energized over this circuit, the relay R3240 operates to complete, at RA3245, a holding circuit for itself, this holding circuit extending from ground at RA3141 by way of C3179, RA3245 and the upper winding of R3240 to battery. At RA3244, the relay R3240, upon operating, completes a path for impressing ground potential upon the control conductor C3482, thereby to mark the line 60 as busy and to prevent this line from being seized by another of the numerical switches provided in the exchange C. The last-mentioned path extends from ground at RA3141 by way of C3179, RA3244 and the wiper 3253 to the control conductor C3482. At RA3246, the relay R3240 opens a point in the above-traced circuit for energizing the operating magnet 3257 of the rotary switch 3250. At RA3247, the relay R3240 opens a point in the circuit, traced hereinafter, for impressing busy tone voltage upon the established communication circuit extending to the operator's position in the exchange B. At RA3243, the relay R3240 prepares a circuit, traced hereinafter, for energizing the switching-through relay R3100, this circuit being held open at the wiper 3252 due to the fact that the contact of the con-

tact set 3273 which corresponds to the line 60 is left unwired. At RA3241, RA3242 and RA3248, the relay R3240 completes a circuit for projecting ringing current over the called line to energize the signal device provided at the called substation T₅ and also a circuit for projecting ring-back tone current back over the communication circuit extending to the operator's telephone set in the exchange B. The circuit traversed by the ringing current may be traced as extending from one terminal of the ring current source, not shown, by way of the winding of the slow-acting ring cut-off relay R3230, RA3226, RA3231, C3174, RA3101, C3175, RA3241, the wiper 3251, C3481, RA3451, the pulsing springs embodied in the calling device 3493, the springs 3456 and 3455, the condenser 3491, the windings of the ringer 3460, ground, and the exchange battery back to the opposite terminal of the ringing current source. The resulting operation of the ringer 3460 indicates to the called subscriber at the substation T₅ that an incoming call should be answered. The ungrounded terminal of the ringing current source is effectively connected to the trunk line conductor C2890 over a path including the winding of R3230, RA3226, RA3242, the condenser 3281, C3176, the condenser 3151' and RA3102, whereby the usual ring-back tone signal is transmitted to the operator located at the operator's position in the exchange B.

When ground potential is impressed upon the control conductor C3482, the cut-off and lock-out relays R3440 and R3430, respectively, are caused to operate in the order named. The cut-off relay R3440, upon operating, disconnects the windings of the line relay R3400 from the conductors of the line 60 and completes at RA3444 a path for impressing ground potential upon the control conductor C3487. The lockout relay R3430, upon operating, opens, at RA3432, a point in the previously traced path for impressing ground potential upon the distributor start conductor C3433 and prepares a point in its own holding circuit.

The manner in which the duplex lines extending to the exchange are terminated in the bank contacts of the numerical switches provided in the exchange C is identical with the mode of terminating subscribers' lines of the duplex type in the numerical switches located in the exchange B. Thus, the duplex line 60 is terminated at two sets of contacts in the bank contact field of the rotary switch 3250, the line conductors C3481 and C3483 being reversely connected in the respective two contact sets. Hence, selection of the substations T₅ and T₆ associated with the line 60 is accomplished by dialing different units digits, each corresponding to the line 60 but designating different ones of the two enumerated substations. For example, if the substation T₆ is the called substation rather than the substation T₅, a different units digit is dialed at the operator's position so that the wipers of the switch 3250 are operated into engagement with the second set of contacts terminating the line 60. In this latter case, the wiper 3251 is left standing in engagement with the contact terminating the line conductor C3483 rather than the line conductor C3481 so that, during the ringing operation, ringing current is conducted by way of C3483, RA3471, the pulsing springs of the calling device 3494, the springs 3476 and 3475, the condenser 3492, and the windings of the signal device 3480 to energize this signal device rather

than by way of the windings of the signal device 3460 provided at the substation T₅.

To answer the call as routed to the substation T₅, the called subscriber lifts the receiver 3458 from its supporting hook, thereby to operate the springs 3455 and 3456 out of engagement and to move the hook switch arm 3457 into engagement with the associated contact 3456. When the last-mentioned operation is performed, a circuit is completed for energizing the slow-to-release lock-out relay R3470 in series with the slow-acting ring cut-off relay R3230, this circuit extending from ground at RC3473 by way of RA3472, the winding of R3470, the transmitter 3459, the receiver 3458, the hook switch arm 3457, the contact 3456, the pulsing springs of the calling device 3493, RA3451, C3481, the wiper 3251, RA3241, C3175, RA3101, C3174, RA3231, RA3226 and the winding of R3230 to battery. The relay R3470 operates when energized over the circuit just traced and, upon operating, completes an alternative circuit for energizing its winding in series with the winding of R3230. This alternative circuit may be traced as extending from ground at RA3228 by way of RA3239', C3196, RA3106, C3199, RA3248, the wiper 3256, C3483, RA3471, RA3472, the winding of R3470, the transmitter 3459, the receiver 3458, the hook switch arm 3457, the spring 3456, the pulsing springs of the calling device 3493, RA3451, C3481, the wiper 3251, RA3241, C3175, RA3101, C3174, RA3231, RA3226 and the winding of R3230 to battery. When energized over the circuit just traced, the relay R3230 operates to complete, at RA3231, an obvious circuit for energizing the relay R3235. The last-mentioned relay, upon operating, completes, at RA3238, a holding circuit for itself, which holding circuit may be traced as extending from ground at RA3141 by way of C3179, RA3238 and the winding of R3235 to battery. At RA3239, the relay R3235 opens a point in the circuit, traced hereinafter, for energizing the relay R3225. At RA3236, the relay R3235 opens a point in the path, traced above, for applying ground potential to the ringing and tone apparatus start conductor C3131'. At RA3237, the relay R3235 opens a point in the above-traced circuits traversed by the ringing and ring-back tone currents and also a point in the above-traced operating circuit for the ring cut-off relay R3230, causing the last-mentioned relay to restore. At RA3237 and RA3239' and their respective associated working contacts, the relay R3235 completes a circuit for energizing the windings of R3110, R3470 and the impedance element 3216 in series, which circuit may be traced as extending from ground at the upper terminal of the winding R3110 by way of this winding, C3198', RA3215, RA3239', C3196, RA3106, C3199, RA3248, the wiper 3256, C3483, RA3471, RA3472, the winding of R3470, the transmitter 3459, the receiver 3458, the hook switch arm 3457, the contact 3456, the pulsing springs of the calling device 3493, RA3451, C3481, the wiper 3251, RA3241, C3175, RA3101, C3174, RA3231, RA3211 and the winding of the impedance element 3216 to battery. The current traversing the circuit serves to maintain the relay R3470 operated and also to energize the transmitter 3459. It will be observed that, with the relay R3470 operated, the apparatus provided at the substation T₅ is effectively locked out of service and thus the connection is guarded against intrusion through the attempted initiation of a call at the substation T₅.

until the connection extending to the substation T₅ is cleared out.

The relay R3110 operates when energized in series with the relay R3470 over the above-traced circuit. Upon operating, the relay R3110 functions to reverse battery back over the trunk line 61 to the repeater illustrated in Figs. 26 and 27, so that the two windings of the relay R2700 are cumulatively energized. More particularly, when the relay R3110 operates, the lower winding of R2700 is energized over a circuit which may be traced as extending from ground at the lower terminal of the lower winding of R3125 by way of this winding, the lower winding of R3120, RA3111, RA3112, RA3102, C2830, RA2711, 15 C2615, the transformer winding 2618, RA2613, C2686, RA2715, the lower winding of R2700, the resistor 2101', the transformer winding 2619, C2695, RA2719, C2891, RA3105, RA3115, RA3114, the upper winding of R3120 and the upper winding of R3125 to battery.

From the foregoing description it will be recalled that only the three relays R2605, R2620 and R2710, embodied in the repeater illustrated in Figs. 26 and 27, are operated at the time the relay R3110 operates to reverse battery back over the trunk line 61. When its two windings are cumulatively energized, the relay R2700 operates to complete, at RA2701, a circuit for energizing the slow-acting relay R2670, which circuit extends from ground at RA2652 by way of C2690, RA2701 and its associated working contact, RA2764, RA2736, C2682, RA2657 and the winding of R2670 to battery. When energized over this circuit, the relay R2670 operates to prepare, at RA2674, a circuit for energizing R2660 and to complete, at RA2672, a circuit extending from ground at RA2642 for energizing the relay R2630. At RA2673, the relay R2670 completes a circuit extending from ground at RA2643 for energizing the slow-acting relay R2645 which latter relay, upon operating, disconnects, at RA2646 and RA2647, the conductors of the trunk line 37 from the line terminals of the repeating transformer windings 2616 and 2617. The relay R2630, upon operating, completes, at RA2632, the above-mentioned circuit for energizing the relay R2660. Also, the relay R2630 connects, at its armatures RA2631 and RA2633, the conductors C1885 and C1886 of the trunk line 37 to opposite terminals of the alternating current source provided in the exchange C. The relay R2660, upon operating, completes, at R2662, the operating circuit for R2655 and, at RA2664, a circuit for energizing the lower winding of R2760. The last-mentioned circuit may be traced as extending from ground at RA2625 by way of 2644, RA2664, C2692, RA2752, RA2765 and the lower winding of R2760 to battery. When its lower winding is energized over this circuit the relay R2760, which is of the two-step type, partially operates to complete, at RA2761, a path for short-circuiting its upper winding, this path extending by way of the grounded conductor C2692, RA2752, RA2765, the upper winding of R2760, 65 RA2761 and RA2762 back to ground at RA2713.

As indicated above, the relay R2655 is energized and operates in response to the operation of R2660. Upon operating, the relay R2655 opens, at RA2667, a point in the above-traced 70 operating circuit for R2670, causing the last-mentioned relay to restore to initiate the sequential restoration of R2660 and R2655 in the order named. When the relay R2660 restores it opens, at RA2664, a point in the above-traced path 75

short-circuiting the upper winding of R2760, permitting the two windings of the last-mentioned relay to be energized in series. The relay R2760 now completes its operation to open, at RA2764, a point in the above-traced operating circuit for R2760 thereby to arrest the cyclic operation of the three relays, R2655, R2660 and R2670. At RA2765 and its associated working contact, the relay R2760 prepares a circuit, traced hereinafter, for energizing the lower winding of R2750. Aside from the circuit operations just described, the operation of the relay R2760 is without effect at this time.

When the relay R2670 restores, in the manner pointed out above, it opens, at RA2673, a point in the operating circuit for R2645 and, at RA2672, a point in the operating circuit for R2630, causing both of these relays to restore. When the two relays R2630 and R2645 restore, the line conductors C1885 and C1886 of the trunk line 37 are disconnected from the alternating current source provided in the exchange C and are reconnected to the line terminals of the repeating transformer windings 2616 and 2617.

When the pulse of alternating current is projected over the conductors of the trunk line 37 to the repeater illustrated in Figs. 17 and 18 in the manner just described, the relay R1815 is energized and operates. At this time, only the three relays R1700, R1705 and R1730, embodied in the repeater shown in Figs. 17 and 18, are operated. Accordingly, when the relay R1815 operates, it completes, at RA1817, a circuit for energizing the lower winding of R1712, this circuit extending from ground by way of RA1817, C1790, RA1737, RA1723, RA1717 and the lower winding of R1712 to battery. The relay R1712 is of the two-step type such that it only partially operates when its lower winding is alone energized. Upon partially operating, the relay R1712 completes, at the "X" contacts associated with RA1713, a path for short-circuiting its upper winding, which path may be traced as extending by way of the grounded conductor C1790, RA1737', RA1723, RA1717, the upper winding of R1712, RA1713 and RA1741 back to ground at RA1733. At the end of the alternating current pulse transmitted, by way of the trunk line 37 to the repeater illustrated in Figs. 17 and 18, the relay R1815 is deenergized and restores. Upon restoring, this relay opens, at RA1817, a point in the above-traced path short-circuiting the upper winding of R1712, permitting the two windings of the last-mentioned relay to be energized in series. The relay R1712 now completes its operation to open, at RA1717 and its associated resting contact, a point in the above-traced circuit for energizing its lower winding and to prepare, at RA1717 and its associated working contact, a circuit, traced hereinafter, for energizing the lower winding of R1720. At RA1714 and RA1715, the relay R1712, upon fully operating, reverses battery back over the loop extending through the operated incoming connector switch illustrated in Figs. 12 and 13 and the trunk line 30 to the operator's position equipment, illustrated in Fig. 7. More particularly, when the relay R1712 operates, the upper winding of the supervisory relay R1790 is energized over a circuit which may be traced as extending from ground at the upper terminal of the lower winding of R1705, by way of this winding, the lower winding of R1710, RA1715, C1378, the wiper 1371, C1262, RA1201, C853, the switch springs 816 and 817, RA1782, RC1783, the transformer winding 175, RA1791, the

upper winding of R790, the resistor 797, the transformer winding 776, RC786, RA785, the switch springs 822 and 821, C854, RA1206, C1278, the wiper 1372, C1380, RA1714, the upper winding of R1710 and the upper winding of R1705 to battery. The direction of current flow over this circuit is such that the two windings of the relay R790 are cumulatively energized and the relay operates. Upon operating, the relay RA790 opens, at RA791, a point in the previously traced circuit by way of which the supervisory lamp 511 and the relay R530 are being held energized in series, causing the lamp 511 to be extinguished and the relay R530 to restore to open, at RA531, a point in the operating circuit for the audible signaling device 535.

As pointed out previously, the operator at the operator's position in the exchange B, after dialing the appropriate line selecting digits to cause the desired line to be selected, may utilize one of the link lines, such, for example, as the line 552, to establish a link or jumper connection between the calling and called talking circuits and release her telephone substation apparatus for use in the completion of other calls. Usually the establishment of the link connection is performed after the dialing operation is completed and when the call is answered. To establish the link connection between the calling and called talking circuits in the case here being considered, the operator may actuate the two connecting switches 658 and 751 to the off-normal position. When the switch 658 is operated to its off-normal position, the springs 664 and 659 are closed to connect the line terminals of the repeating transformer 650 to the link line conductors C688 and C689.

At the springs 663, an alternative circuit is prepared for energizing the supervisory lamp 511 in series with the relay R530 when the switch 658 is operated to its off-normal position. Also, the springs 661 are closed to complete an obvious alternative circuit for maintaining the busy lamp 698 energized. At the springs 660 an alternative circuit extending by way of RA692 is completed for maintaining the relay R695 energized. When the switch 751 is operated to its off-normal position, the springs 758 and 762 are closed to connect the line conductors C688 and C689 of the link line 552 to the line terminals of the transformer windings 772 and 773 embodied in the repeating transformer 771, thereby to complete the desired jumper connection between the calling and called talking circuits. Also, when the switch 751 is moved to its off-normal position, the springs 759 are closed to prepare the above-mentioned alternative circuit for energizing the supervisory lamp 511 in series with the relay R530. At the springs 760 an obvious alternative circuit is completed for maintaining the busy lamp 763 energized and at the springs 761 an obvious alternative circuit is completed for maintaining the relay R795 energized. Following the operation of the connecting switches 658 and 751 to the off-normal position to establish the desired jumper connection, the call and answer key switches 666 and 764 may be returned to normal, thereby to disconnect the operator's substation equipment from the established connection. It will be noted that, when these two switches are restored to normal, the line conductors C541 and C548 of the link line 553 are disconnected from the line terminals of the two repeating transformers 650 and 771. Also, the circuit for supplying energizing current to the

transmitter 500 is interrupted at the springs 667 and 765. At the springs 670 of the switch 666, the multiple circuit for energizing the busy lamp 698 is opened, while, at the springs 671, the operating circuit for the relay R695 is interrupted. At the springs 767 of the switch 764, a point is opened in the above-traced operating circuit for the relay R780 and, at the springs 768, a point is opened in the multiple circuit for energizing the busy lamp 763. Finally at the springs 769, the operating circuit for the relay R795 is interrupted, this relay being held energized over the holding circuit, described above, which is completed in response to operation of the connecting switch 751 to its off-normal position. Following the completion of the jumper connection in the manner just described, the two busy lamps 698 and 763 are both energized to indicate that the respective associated trunk lines 831 and 832 are busy. Since the relay R695 is operated, the line signal lamp 679 is deenergized at this time. It will be apparent from the foregoing description that the supervisory lamp 511 and the relay R530 are maintained energized over the circuit traced previously, until such time as the call is answered at the called substation, this circuit being interrupted, in the manner described above, in response to the operation of the relay R790. Thus, when the desired talking connection between the calling and called substations is fully completed, only the two busy lamps 698 and 763 are energized.

If, following the completion of a talking connection between the calling and called substation, in a manner just described, the called subscriber desires to resignal the operator in the exchange B, he may do so by momentarily operating the hook switch provided at the substation T₅ between its two operating positions one or more times. Each time the hook arm 3451 is moved to its normal position to disengage the contact 3456, the loop circuit extending to the called substation T₅ is interrupted and the relays R3470 and R3110 are deenergized, causing the last-mentioned relay to restore. Obviously, if the hook switch arm 3457 is held in its normal position for too long a time interval, the relay R3470 also restores. When, however, the loop circuit is recompleted by releasing the hook switch arm 3457 so that it again engages the contact spring 3456, the two relays R3110 and R3470 are again energized in series with each other and with the impedance element 3216.

The relay R3110 restores each time the hook switch provided at the called substation T₅ is returned to its normal position and, upon restoring, reverses battery back over the trunk line 61 so that the polarity of the current traversing the lower winding of the relay R2700 is reversed with respect to the polarity of the current traversing the upper winding of this relay. Thus, the relay R2700 is caused to restore to complete, at RA2701, another alternative circuit for energizing the slow-acting relay R2670, this circuit extending from ground at RA2652 by way of C2690, RA2701 and its associated resting contact, RA2764 and its associated working contact, RA2736, C2682, RA2657 and the winding of R2670 to battery. When energized over this circuit, the relay R2670 operates to initiate the sequence of operations described previously; that is, it completes the operating circuit for R2660 and completes the previously traced operating circuits for R2630 and R2645. When the two

last-mentioned relays operate, the conductors of the trunk line 37 are disconnected from the line terminals of the transformer windings 2616 and 2617, and are again connected to opposite terminals of the alternating current source provided in the exchange C, whereby an alternating current pulse is transmitted by way of the trunk line 37 to the repeater illustrated in Figs. 17 and 18. When the relay R2660 operates in response to the operation of R2670, it completes, at RA2664, a circuit for energizing the lower winding of R2750, which circuit extends from ground at RA2625 by way of R2644, RA2664, C2692, RA2752, RA2765 and the lower winding of R2750 to battery. The relay R2750 is of the two-step type such that it operates to close only the "X" contacts associated with RA2751 when its lower winding is alone energized. When these "X" contacts are closed, a path is completed for short-circuiting the upper winding of R2750, this path extending from ground at RA2713 by way of RA2726, RA2751, the upper winding of R2750, RA2765, RA2752, C2692, RA2664 and RA2644 back to ground at RA2625. The relay R2660, upon operating, also completes, at RA2662, the operating circuit for R2655, which latter relay, upon operating, opens at RA2651, the operating circuit for R2670, thereby to initiate the sequential restoration of the three relays R2670, R2660 and R2655. When the relay R2660 restores, it opens, at RA2664, a point in the above-traced path short-circuiting the upper winding of R2750, permitting the two windings of the last-mentioned relay to be energized in series. The relay R2750 now completes its operation to open, at RA2752, a further point in its operating circuit and to complete, at RA2753, an obvious circuit for energizing the slow-to-operate relay R2725. When the relay R2725 operates it opens, at RA2726, a point in the common portion of the holding circuits for the two relays R2750 and R2760, causing both of these relays to restore and open further points in their respective holding circuits. The relay R2760, upon restoring, also opens, at RA2764 and its associated working contact, a point in the above-traced alternative operating circuit for the relay R2670, causing the last-mentioned relay to remain in its restored position. With R2670 restored, the two relays R2660 and R2655 are prevented from reoperating and the respective operating circuits for R2630 and R2645 are interrupted. More particularly, when the relay R2670 first restores to initiate the sequential restoration of R2660 and R2655, the two relays R2630 and R2645 also restore to disconnect the conductors of the trunk line 37 from the alternating current source provided in the exchange C and to reconnect these conductors to the repeating transformer windings 2616 and 2617. Thus, the pulse of alternating current transmitted by way of the trunk line 37 to the repeater shown in Figs. 17 and 18 is terminated.

When the alternating current source provided in the exchange C is connected to the conductors of the trunk line 37, the alternating current relay R1815 embodied in the repeater illustrated in Figs. 17 and 18 is energized and operates to complete, at RA1817, the previously mentioned circuit for energizing the lower winding of the relay R1720, it being pointed out that the relays R1700, R1705, R1712 and R1730 are the only ones of the relays embodied in the indicated repeater which are operated at the time the relay R1815 operates. The circuit for energizing the

lower winding of the relay R1720 may be traced as extending from ground at RA1817 by way of C1790, RA1737, RA1723, RA1717 and the lower winding of R1720 to battery. The relay R1720 is of the two-step type such that it partially operates to close only the "X" contacts associated with RA1721 when its lower winding is alone energized. When these "X" contacts are closed, the relay R1720 completes a path for short-circuiting its upper winding, which path may be traced as extending from ground at RA1733 by way of RA1741, RA1721, the upper winding of R1720, RA1717, RA1723, RA1737 and C1790 back to ground at RA1817. When the alternating current pulse transmitted by way of the trunk line 37 is terminated in the manner explained above, the relay R1815 restores to open, at RA1817, a point in the path short-circuiting the upper winding of R1720, permitting the two windings of the last-mentioned relay to be energized in series. The relay R1720 now fully operates to complete, at RA1722, an obvious operating circuit for the slow-to-operate relay R1740. The relay R1740, upon operating, opens, at RA1741, a point in the common portion of the respective holding circuits for R1712 and R1720, causing both of these relays to restore. The relay R1712, upon restoring, reverses the direction of current flow over the previously traced circuit including the upper winding of the supervisory relay R790, causing the last-mentioned relay to restore to recomplete, at RA1791, the previously traced circuit for energizing the supervisory lamp 511 and the relay R530 in series.

As pointed out above, when the hook switch arm 3457 is released, after momentarily being operated to its normal position, it is moved into engagement with the contact spring 3456 to recomplete the previously traced circuit for energizing the relay R3470 in series with the relay R3110, causing both of these relays to reoperate. The relay R3110, upon reoperating, again reverses battery back over the trunk line 61 to the repeater illustrated in Figs. 26 and 27, whereby the direction of current flow through the lower winding of R2700 is again reversed. The two windings of R2700 are now cumulatively energized and this relay is caused to reoperate to recomplete, at RA2701, the previously traced alternative operating circuit for the relay R2670. The four relays R2630, R2645, R2655 and R2660 respond to the reoperation of R2670 in the exact manner explained above; that is, the relay R2645 opens a point in the link circuit extending by way of the trunk line 37 to the repeater illustrated in Figs. 16 and 17; the relay R2630 connects the line conductors of the trunk line 37 to the alternating current source provided in the exchange C; and the relay R2660 reoperates to complete, at RA2664, the previously traced circuit for energizing the lower winding of R2760. When its lower winding is energized, the relay R2760 again partially operates to recomplete, at the "X" contacts associated with RA2761, the previously traced path for short-circuiting its upper winding. The relay R2655, upon operating, opens, at RA2657, the operating circuit for R2670, thereby to initiate the sequential restoration of R2670, R2660, and R2655 in the order named. Upon restoring, the relay R2670 opens the respective operating circuits for R2630 and R2645, thereby to terminate the pulse of alternating current which is transmitted by way of the trunk line 37 to the repeater shown in Figs. 17 and 18. The relay R2660, upon restoring,

opens, at RA2664, a point in the path short-circuiting the upper winding of R2760, causing the last-mentioned relay to complete its operation to open, at RA2764, a point in the operating circuit for the relay R2670, thus preventing the three relays R2670, R2660 and R2655 from continuing their cyclic operation. Also, the relay R2760, upon fully operating, reprepares the previously traced circuit for energizing the lower winding of R2750. Following the operation of R2760, the relay equipment embodied in the repeater illustrated in Figs. 26 and 27 is returned to the condition which prevailed when the connection was initially established between the calling and called substations.

The relay R1815, embodied in the repeater illustrated in Figs. 17 and 18, responds to the alternating current pulse transmitted by way of the trunk line 37 in response to the completion of the loop circuit extending to the called substation by reoperating to recomplete, at RA1817, the previously traced circuit for energizing the lower winding of R1712. The relay R1712 again partially operates to complete, at RA1713, the previously traced path for short-circuiting its upper winding. At the end of the alternating current pulse, when the relay R1815 restores, this short-circuiting path is interrupted at RA1817, permitting the two windings of R1712 to be energized in series. The relay R1712 now completes its operation to again reverse the direction of current flow through the upper winding of the supervisory relay R790, causing the last-mentioned relay to reoperate. Upon reoperating, the relay R790 opens, at RA791, a point in the above-traced circuit for energizing the supervisory lamp 511 in series with the relay R530, thereby to extinguish the lamp 511 and to terminate the operation of the signal device 535.

It will be apparent from the foregoing description that the sequence of operations just described occurs each time the hook switch provided at the called substation T₅ is operated from its off-normal position to its normal position and then back to its off-normal position. Hence, if the hook switch is operated up and down a number of times, the supervisory lamp 511 and the signal device 535 provided at the operator's position are caused intermittently to operate, thereby to indicate to the operator that she is being recalled by one of the parties conversing over the connection in which the link line 552 is included. In order to reenter the connection, it is only necessary for the operator to actuate one of the two call and answer key switches 764 and 666 to the off-normal position, thereby to reconnect her telephone substation apparatus to the established talking circuit in an obvious manner so that she may converse with the called party to ascertain what service or information is desired.

As indicated previously, if the desired called substation is associated with a line of the multiplex type extending to the exchange C, it is necessary to transmit a third series of impulses by way of the incoming connector switch illustrated in Figs. 31 and 32 to the station selecting apparatus associated with the selected called line. In order to condition the control apparatus of the incoming connector switch to repeat the impulses to the station selecting apparatus associated with a subscriber's line of this type, the relay R3225 is provided, which relay is arranged to operate immediately the called multiplex line

is selected. More particularly, each of the contacts included in the contact level 3275 and corresponding to a line of the multiplex type is connected to ground so that, if the wiper 3254 is left standing in engagement with the contact of a set terminating a line of the multiplex type, the relay R3225 is energized over a circuit extending by way of the wiper 3254, RA3239 and the winding of R3225 to battery. Upon operating, the relay R3225 opens, at RA3226, a point in the incomplete circuit for impressing ringing voltage upon the conductors of the called line. At RA3228 and its associated working contact, the relay R3225 prepares a path for impressing negative battery potential upon the positive line conductor of the selected called line. Shortly after the line is selected, the line switching relay R3240 is caused to operate in the manner explained previously, provided the line is idle. Upon operating, the relay R3240 completes the above-mentioned path for impressing negative battery potential upon the positive side of the selected line. This path extends from the negative terminal of the exchange battery by way of the resistor 3117, RA3128, C3193, RA3228, RA3239', C3196, RA3106, C3199, RA3248 and the wiper 3256 to the positive line conductor of the selected called line. At RA3244, the relay R3240 also completes the previously traced path for impressing ground potential upon the control conductor of the selected multiplex line, whereby the station selecting apparatus associated with this line is seized and conditioned to operate in response to the impulses comprising the third series of impulses transmitted to the incoming connector switch and the fifth digit dialed at the operator's position in the exchange B. The line relay R3125 responds to the impulses of this digit by repeatedly opening, at RA3128, the above-traced path for applying negative battery potential to the positive side of the selected called line, and the station selecting apparatus associated with the selected line responds to the battery pulses by connecting the line conductors of the called line to the substation apparatus provided at the desired called substation in the usual manner. At the beginning of the first impulse of the impulse series the relay R3125 restores to complete the above-traced circuit for energizing the winding of R3160 in parallel with the lower winding of R3170, causing both of these relays to reoperate. At this time, the branch of this circuit which includes the winding of the rotary switch operating magnet 3257 is interrupted at the operated armature RA3246 of the switching-through relay R3240. Upon operating, the relay R3160 completes the operating circuit for R3165, which latter relay, in turn, operates to complete an alternative circuit for energizing the busy relay R3200. This alternative circuit may be traced as extending from ground at RA3141 by way of C3179, RA3244, C3184, RA3156, RA3166, RA3167, C3183 and the lower winding of R3200 to battery. The relay R3200, upon operating, prepares, at RA3201, its holding circuit as traced above and prepares, at RA3204, a circuit, traced hereinafter, for energizing the relay R3220. At the end of the third series of impulses transmitted to the incoming connector switch, the line relay R3125 is held operated and the three relays R3160, R3165 and R3170 are caused to restore in the manner explained previously. Upon restoring, the relay R3165 completes the above-traced holding cir-

cuit for the busy relay R3200. The relay R3165, upon restoring, also completes the above-mentioned circuit for energizing the relay R3220, this circuit extending from ground at RA3141 by way of C3179, RA3244, C3184, RA3156, RA3166, C3181, RA3221, RA3204 and the winding of R3220 to battery. When energized over this circuit, the relay R3220 operates to complete, at RA3221, the previously traced circuit for connecting the ringing current source to the negative line conductor of the selected called line, thereby to energize the signal device provided at the called substation. The operation of the relay R3220 to complete the previously traced ringing current circuit is also effective to cause ringing current to be projected over the established talking loop extending to the operator's position in the exchange B, thereby to signal the operator that the desired called substation is being rung.

When the call is answered at the called substation, ground potential is impressed upon the negative line conductor of the called line to complete a circuit for energizing the ring cut-off relay R3230, this circuit extending by way of the grounded line conductor, the wiper 3251, RA3241, C3175, RA3101, C3174, RA3231, RA3221 and the winding of R3230 to battery. When energized over this circuit, the relay R3230 operates to complete, at RA3231, the operating circuit for the relay R3235, which latter relay, upon operating, completes, at RA3238, its holding circuit and opens, at RA3239, the operating circuit for the relay R3225, causing the last-mentioned relay and the relays R3220 and R3230 to restore in the order named. At RA3231 and RA3239, the relay R3235 completes a circuit for applying talking battery voltage to the conductors of the selected called line, one branch of this circuit extending from the negative terminal of the exchange battery by way of the winding of the line balancing impedance element 3216, RA3211, RA3237, C3174, RA3101, C3175, RA3241 and the wiper 3251 to the negative line conductor of the called line, and the other branch extending from the positive or grounded side of the exchange battery by way of the winding of R3110, C3198, RA3215, RA3239, C3196, RA3106, C3199, RA3248 and the wiper 3256 to the positive conductor of the selected called line. The relay R3110 is energized over this circuit and operates its armatures RA3111, RA3112, RA3114 and RA3115 to reverse battery back over the loop circuit extending to the repeater illustrated in Figs. 26 and 27, thereby to cause a supervisory pulse of alternating current to be transmitted by this repeater to the switching equipment located in the distant exchange B in the manner previously described. The operated switching equipment in the exchange B responds to the alternating current pulse by operating to open the circuit for energizing the supervisory lamp provided at the operator's position in this exchange and associated with the link line being used in the connection, all in the manner explained previously. The manner in which a connection routed to a substation connected to a line of the multiplex type is released is pointed out with particularity hereinafter.

As indicated previously, if the wipers of the rotary switch 3250 embodied in the incoming connector switch illustrated in Figs. 31 and 32 are operated into engagement with the contacts terminating the conductors of a desired line at a time when the line is busy, busy tone is re-

turned over the calling loop circuit to the operator in the distant exchange B to indicate that the desired connection can not immediately be obtained. Thus, if the call originating at the operator's position in the exchange B and intended for substation T₅ associated with the line 60 is initiated at a time when the line 60 is busy, the slow-to-release busy relay R3200 is caused to operate immediately the wipers of the switch 3250 are operated into engagement with the contacts terminating the conductors of the called line. More particularly, when the called line 60 is busy, ground potential is present upon the control conductor C3482 thereof. Accordingly, the busy relay R3200 is energized over a circuit extending by way of C3482, the wiper 3253, C3184, RA3156, RA3166, RA3167, C3183 and the lower winding of R3200 to battery. When its lower winding is energized over this circuit, the relay R3200 operates to prepare, at RA3201, a holding circuit for itself and to prepare, at RA3204, a point in the above-traced operating circuit for the relay R3220. At RA3201 and its associated resting contact, the relay R3200 opens a point in the circuit, traced previously, for energizing the lower winding of the line switching relay R3240. At RA3203, the relay R3200 opens a point in the circuit, traced previously, by way of which the lower winding of R3170, the winding of R3160 and the winding of the rotary switch operating magnet 3257 are energized during impulsion, thereby to prevent further operation of the calling device provided at the operator's position from effecting further operation of the rotary switch 3250. At RA3205, the relay R3200 effectively connects the busy tone conductor C3259 to the line conductor C3198 of the trunk line incoming to the connector switch of Figs. 31 and 32, thereby to cause busy tone current to be projected back over the established talking circuit through the receiver provided at the operator's telephone station located in the exchange B. The resulting busy tone signal indicates to the operator that the line extending to the called substation is busy. Shortly following the operation of the busy relay R3200, the three relays R3160, R3165 and R3170 are caused to restore in the manner explained previously. The relay R3165, upon restoring, completes the above-mentioned holding circuit for the busy relay, this circuit extending from ground at RA3141 by way of RA3151, C3180, RA3201, RA3212, C3182, RA3167, C3183 and the lower winding of R3200 to battery. Thus, the busy relay is held energized and remains operated.

As indicated previously, provisions are made whereby, on a toll call routed by way of an operator's position in the exchange B or the operator's position in the exchange C, a talking connection may be established to the called line even though the line is busy. Thus, in the call under consideration, if the operator in the exchange B desires to offer the call to one of the parties conversing over the previously established connection, she may cause the apparatus utilized in the partially completed connection to operate and set up a talking circuit bridging the previously established connection by momentarily operating the toll offering switch 753 to its off-normal position to apply ground potential to the line conductor C854 of the trunk line 30. When ground potential is applied to C854, the respective lower windings of R1705 and R1710 are short-circuited over a path which may be traced as extending by way of the grounded conductor

C854, RA1206, CI278, the wiper 1372, CI380, RA1715, the lower winding of R1710 and the lower winding of R1705 back to ground. When its lower winding is short-circuited over this path, the differentially wound relay R1710 operates to complete, at RA1711, a circuit for energizing the upper winding of R1724, this circuit extending from ground at RA1733 by way of RA1711 and the upper winding of R1724 to battery. At RA1725, the relay R1724, upon operating, completes a holding circuit for itself, which holding circuit extends from ground at RA1733 by way of RA1725 and the upper winding of R1724 to battery. Shortly following the operation of R1724 and when the toll offering switch 153 is released to open the above-traced path short-circuiting the lower winding of R1710, the two windings of the last-mentioned relay are again energized in opposition, and this relay restores to open, at RA1711, the operating circuit, as traced above, for the relay R1724. At RA1729, the relay R1724, upon operating, applies ground potential to the second contact of the outer row of contacts embodied in the minor switch 1710, thus preparing a circuit, traced hereinafter, for energizing the lower winding of the relay R1724. At RA1726, RA1727 and RA1728, respectively, the relay R1724, upon operating, completes operating circuits for the three relays R1830, R1840 and R1820; the operating circuit for the relay R1830 extending from ground at RA1726 by way of RA1734, CI1779 and the upper winding of R1830 to battery; the operating circuit for R1840 extending from ground at RA1727 by way of RA1735, CI1781 and the winding of R1840 to battery; and the operating circuit for R1820 extending from ground at RA1728 by way of RA1737, CI1784 and the winding of R1820 to battery. The relay R1840, upon operating, connects the line conductors CI1885 and CI1886 of the trunk line 37 to the alternating current source provided in the exchange B, and the relay R1820 disconnects the line terminals of the repeating transformer windings 1878 and 1879 from the enumerated line conductors of the trunk line 37 to prevent the alternating current from being returned to the operator's telephone set, all in the manner previously explained. The relay R1830, upon operating, prepares, at RA1831, a circuit for energizing the operating magnet 1772 of the minor switch 1770 and prepares, at RA1833, an operating circuit for the relay R1805. At RA1832, the relay R1830 completes a circuit extending by way of RA1812 for energizing the slow-acting relay R1800. When the relay R1800 operates, it completes, at RA1801, a holding circuit for R1830 and completes, at RA1804, the previously mentioned circuit for energizing R1805. The holding circuit for the relay R1830 extends from ground at RA1831 by way of RA1801 and the upper winding of R1830 to battery and the circuit for energizing the relay R1805 extends from ground at RA1833 by way of RA1804 and the winding of R1805 to battery. The relay R1805, upon operating, shunts, at RA1806, the armature RA1801 to provide a multiple holding circuit for R1830 and completes, at RA1807, the operating circuit for the relay R1810. The relay R1810, upon operating, opens at RA1812, the operating circuit for R1800 as traced above, thereby to initiate the sequential restoration of the two relays R1805 and R1810. Thus, the cyclic operation of the three relays R1800, R1805 and R1810 is initiated. During each cycle of operation of the three relays R1800, R1805 and R1810 and

when the relay R1810 operates, the above-mentioned circuit for energizing the operating magnet 1772 embodied in the minor switch 1770 is completed, this circuit extending from ground at 5 RA1831 by way of RA1811, CI1797 and the winding of the magnet 1772 to battery. Obviously, this operating circuit is also interrupted during each cycle of operation of the three enumerated relays when the relay R1810 restores. Thus, during 10 each cycle of operation of the three relays R1800, R1805 and R1810, the wiper 1771 of the switch 1770 is stepped one step so that, at the end of the second cycle of operation of the three relays noted, this wiper engages the respective 15 second contacts of the bank contact field embodied in the switch 1770. When the wiper 1771 is operated to this position, the above-mentioned circuit is completed for energizing the lower winding of R1724, which circuit extends from 20 ground at RA1729 by way of the wiper 1771 and the lower winding of R1724 to battery. The relay R1724 is differentially wound so that it restores when both of its windings are energized. At RA1725, the relay R1724, upon restoring, 25 interrupts its holding circuit as traced above. Upon restoring, the relay R1724 also opens, at RA1721 and RA1728, respectively, the above-traced operating circuits for the relays R1840 and R1820, causing both of these relays to restore to terminate 30 the alternating current pulse transmitted over the trunk line 37 and to reconnect the conductors of this trunk line to the line terminals of the repeating transformer windings 1878 and 1879. The relay R1724, upon restoring, also 35 opens, at RA1726, a point in the above-traced operating circuit for the relay R1830, causing the last-mentioned relay to restore when the two relays R1800 and R1805 restore to open the holding circuit for R1830. When the relay R1830 40 falls back, it opens points in the respective operating circuits for R1800 and R1805, thereby to arrest the cyclic operation of these two relays and the relay R1810. It is pointed out that, when the wiper 1771 of the minor switch 1770 is stepped to 45 its first off-normal position, the off-normal springs 1774 are closed to prepare a circuit for energizing the release magnet 1773. This circuit is completed in response to the restoration of R1830 and extends from ground at RA1831 by 50 way of CI1780, the off-normal springs 1774 and the winding of the magnet 1773 to battery. When energized over this circuit, the magnet 1773 attracts its operating armature, not shown, to cause the wiper 1771 of the switch 1770 to be 55 returned to its home position in the usual manner.

From the foregoing description, it will be apparent that the duration of the alternating current pulse transmitted by way of the trunk line 37 to the repeater illustrated in Figs. 26 and 27 is primarily determined by the time required for the wiper 1771 of the minor switch 1770 to be operated to its second off-normal position. More particularly, the duration of this pulse is of intermediate length as compared with the short seizing pulse transmitted over the trunk line 37 in the manner described above and the long release pulse which is transmitted over the trunk line 37 to initiate the release of the repeater illustrated in Figs. 26 and 27 when the connection is cleared out at the operator's position in the exchange B.

The alternating current relay R2650 responds to the alternating current pulse transmitted over the trunk line 37 in the manner just described

by operating to open, at RA2652 and its associated resting contact, the previously traced holding circuit for the slow-to-release relay R2605. At RA2652 and its associated working contact, the relay R2650 completes the previously traced circuit for energizing the lower winding of the relay R2600 and the winding of the slow-acting relay R2705 in parallel. At RA2706, RA2707 and RA2708, the relay R2705 prepares paths, traced hereinafter, for applying ground potential to each of the two line conductors C2675 and C2695. The relay R2600, upon operating, prepares, at RA2601, a point in the operating circuit for R2620; prepares, at RA2603, the circuit for energizing its own upper winding; and completes, at RA2602, the previously traced path for short-circuiting the lower winding of R2610.

When the relay R2605 restores in response to the operation of the relay R2650, it completes, at RA2608, a circuit for energizing the lower winding of the relay R2640, which circuit may be traced as extending from ground at RA2625 by way of RA2608 and the lower winding of R2640 to battery. The relay R2640 now operates to prepare, at RA2641, the operating circuit for the rotary switch operating magnet 2787 and to initiate the cyclic operation of the three relays R2670, R2660 and R2655, in the manner explained previously. During each cycle of operation of these three relays, the magnet 2787 is energized and deenergized so that the wiper 2786 of the minor switch 2785 is operated away from its home position. When the wiper 2786 is operated off-normal, the off-normal springs 2789 are closed to prepare the operating circuit for the release magnet 2788. The stepping operation of the minor switch 2785 continues until the alternating current pulse being transmitted by way of the trunk line 37 is ended. At the conclusion of this pulse, the alternating current relay R2650 is deenergized and restores to open, at RA2652, a point in the above-traced circuit for energizing the lower winding of R2600 in parallel with the winding of R2705. During the time interval required for the slow-acting relay R2705 to release after its operating circuit is opened, ground potential is impressed upon each of the line conductors C2675 and C2695 over the paths mentioned above. More particularly, these paths are completed in response to the restoration of R2650 and commonly extend from ground at RA2652 by way of RA2623, RA2607 and C2677 to RA2708 where they divide, one path extending by way of RA2707 to the line conductor C2675, and the other path extending by way of C2681, RA2613, C2686, RA2715, RA2708 and C2685 to the opposite line conductor C2695. Obviously, when the relay R2705 restores its armatures RA2706, RA2707 and RA2708 shortly following the restoration of the alternating current relay R2650, the paths just traced are interrupted. When the relay R2705 restores, an alternative circuit is completed for energizing the slow-to-release relay R2605. this circuit extending from ground at RA2652 by way of RA2623, RA2607, C2677, RA2706, C2676, RA2621 and the winding of R2605 to battery. When energized over this circuit, the relay R2605 reoperates to recomplete its holding circuit, as traced previously, and to interrupt, at RA2608, the above-traced circuit for energizing the lower winding of the relay R2640. Shortly thereafter and when the relay R2660 restores to open the holding circuit for the relay R2640, the last-mentioned relay also restores to open points in the respective operating circuits for the two 75

relays R2670 and R2660 and the operating magnet 2787 of the minor switch 2785. Upon restoring, the relay R2640 also completes the circuit, traced previously, for energizing the release magnet 2788, which magnet, upon operating, causes the wiper 2786 of the minor switch 2785 to be restored to its normal position in the usual manner. When the wiper 2786 is returned to its home position, the off-normal springs 2789 are opened to interrupt the operating circuit for the release magnet 2788.

When the alternating current relay R2650 restores, at the end of the alternating current pulse transmitted over the trunk line 37 and in the manner just described, it opens, at RA2652, a point in the path short-circuiting the lower winding of R2610, permitting this winding to be energized in series with the lower winding of R2600. The relay R2610 now operates to complete, at RA2611, the circuit for energizing the upper winding of the relay R2600. The differentially wound relay R2600 now restores to open, at RA2602, a point in the circuit for energizing its lower winding in series with the lower winding of R2610, thus causing the relay R2610 also to restore. During the interval when the relay R2610 is operated, the loop circuit extending to the incoming connector switch of Figs. 31 and 32 is interrupted at RA2613, but the interruption of this loop circuit is without effect at this time. Following the restoration of the relay R2610, the apparatus embodied in the repeater illustrated in Figs. 26 and 27 is returned to the condition which prevailed before the alternating current control pulse was transmitted thereto.

During the interval when ground potential is applied to the line conductor C2675 in the manner described above, the upper winding of the relay R3120 is energized in series with the upper winding of the relay R3125 over a circuit extending by way of the grounded conductor C2675, RA2711, C2890, RA3102, RA3112, RC3113, the upper winding of R3120 and the upper winding of R3125 to battery. When ground potential is simultaneously applied to the line conductor C2695, the series connected lower windings of the relays R3120 and R3125 are short-circuited over a path which may be traced as extending by way of the grounded conductor C2695, RA2719, C2891, RA3105, RA3115, RC3116, the lower winding of R3120 and the lower winding of R3125 back to ground. Since its lower winding is deenergized in response to the completion of this short-circuiting path, the differentially wound relay R3120 now operates to complete, at RA3121, a circuit for energizing the relay R3210, which circuit may be traced as extending from ground at RA3141 by way of C3179, RA3244, C3187, RA3172, RC3173, C3186, RA3202, C3188, RA3121, C3185 and the winding of R3210 to battery. When energized over this circuit, the relay R3210 operates to complete, at RA3213, a path for short-circuiting the upper winding of R3200, this path extending from the upper terminal of the upper winding of R3200 by way of C3188, RA3121, C3185 and RA3213 to the lower terminal of the upper winding of R3200. The completion of this short-circuiting path renders the relay R3200 slow to release. At RA3212 and its associated resting contact, the relay R3210 opens a point in the previously traced holding circuit for the relay R3200. At RA3212 and its associated working contact, the relay R3210 completes an alternative holding circuit for the relay R3200, this alternative holding circuit extending by way of

the grounded control conductor C3482 of the busy called line 60, the wiper 3253, RA3212, C3182, RA3167, C3183 and the lower winding of R3200 to battery. At RA3214, the relay R3210 opens a point in the previously traced circuit for projecting busy tone current by way of the established circuit extending to the operator's position in the exchange B, thereby to terminate the busy tone signal. At RA3211 and RA3215 and their respective associated resting contacts, the relay R3210 disconnects the line conductors C3176 and C3198, respectively, from the terminals of the impedance element 3216 and the battery reversing relay R3110. At these same armatures and their respective associated working contacts, the relay R3210 connects the indicated line conductors C3176 and C3198 to the line conductors of the selected called line 60 so that a talking connection is completed between the operator's telephone set and each of the two substations being used in the previously established connection. Upon the completion of this talking circuit, the operator may break in upon the ensuing conversation, offer the toll call to the called subscriber and request the parties to hang up so that the toll call may be forwarded to the desired called substation. It will be noted that the bridging connection which is established through the connector switch of Figs. 31 and 32 to the called line includes the two condensers 3151' and 3152' and further that no direct current bridge is placed across the conductors of the called line. Thus, the release of the previously established connection including the called line is in no way affected by the completion of the bridging connection.

As indicated above, when the supervisory pulse of alternating current transmitted by way of the trunk line 37 to the repeater illustrated in Figs. 26 and 27 is terminated, the relay R2705 is caused to restore to open the path by way of which ground potential is applied to each of the two trunk line conductors C2890 and C2891. As a result, the lower winding of the differentially wound relay R3120 is again energized and this relay restores to open, at RA3121, a point in the path short-circuiting the upper winding of the busy relay R3200. The upper winding of the relay R3200 is now energized in series with the winding of R3210 over a circuit which may be traced as extending from ground at RA3141 by way of C3179, RA3244, C3181, RA3172, RC3173, C3186, RA3202, the upper winding of R3200, RA3213 and the winding of R3210 to battery. Following the restoration of the differentially wound relay R3120, no further relay operations occur in the incoming connector switch illustrated in Figs. 31 and 32 until the previously established connection including the desired called line is released.

When the previously established connection is cleared out at both ends thereof, the line circuit associated with the line 60 is caused to restore to normal, in the manner explained subsequently, to remove ground potential from the control conductor C3482 and to impress negative potential upon this control conductor. When ground potential is removed from the control conductor C3482 the lower winding of the busy relay R3200 is deenergized. Following the de-energization of this winding, the busy relay R3200 is only energized by the current traversing its upper winding, such energization being insufficient to maintain the relay operated but being of a value such that the restoration of the relay

is delayed for a substantial time interval. At the end of this time interval, the relay R3200 restores to open, at RA3202, a point in the previously traced circuit for energizing its upper winding in series with the winding of the relay R3210, whereby the last-mentioned relay is caused to restore. At RA3205, the relay R3200 opens a further point in the path for applying busy tone voltage to the talking circuit extending to the operator's position in the exchange B. At RA3204, the relay R3200 opens a point in the incomplete operating circuit for the relay R3223. At RA3201 and its associated resting contact, the relay R3200, upon restoring, completes the previously traced circuit for energizing the lower winding of the line switching relay R3240. When the relay R3240 operates, ringing current is projected over the selected called line for the purpose of energizing the signal device provided at the called substation in the manner explained previously. Also, the relay R3240, upon operating, completes the previously traced circuit by way of which ring-back tone current is projected back over the talking circuit to the operator's telephone set in the exchange B, thereby to signal the operator that the ringing operation is being performed. When the call is answered at the called substation, the desired talking circuit is completed in the exact manner described above. By way of summarizing the relay operations which occur when the call is answered at the called substation, it is pointed out that the two relays R3230 and R3235 are caused sequentially to operate in the order named when the loop circuit extending to the called substation is completed, which relays, upon operating, arrest the ringing operation and complete the talking circuit to the called substation. The relay R3235, upon operating, also completes the operating circuit for the battery reversing relay R3110, which latter relay, upon operating, initiates the operation of the repeater illustrated in Figs. 26 and 27 to transmit a supervisory pulse of alternating current by way of the trunk line 37 to the repeater illustrated in Figs. 17 and 18. The last-mentioned repeater responds to the supervisory pulse of alternating current by reversing battery over the loop extending to the operator's position, whereby the supervisory relay R790 is caused to restore to extinguish the supervisory lamp 511.

The release of the connection established between the substations T₁ and T₅, in the manner hereinbefore explained, is partially under the control of the calling party at the substation T₁ and partially under the control of the operator located at the operator's position in the exchange B. More particularly, the release of the finder-connector link illustrated in Figs. 19 and 20 and by way of which the call is forwarded from the substation T₁ to the operator's position is under the control of the calling subscriber, whereas the release of the operated switching equipment, by way of which the connection is routed from the operator's position to the called substation T₅, is under the control of the operator in the exchange B. In any case, a disconnect signal is given to the operator when the connection is cleared out at either the calling or called substations. Thus, if the calling subscriber at the substation T₁ restores his receiver to its hook, the hook switch arm 2167 is moved out of engagement with the associated spring 2166 to interrupt the previously traced loop circuit by way of which the relay R2110

is being held energized in series with the two windings of **R685**, causing both of these relays to restore. The relay **R685**, upon restoring, completes, at **RA686**, the previously traced circuit extending by way of the switch spring **663** for energizing the supervisory lamp **511** in series with the relay **R530**, thereby to cause the lamp **511** to be illuminated and the signal device **535** to operate. The resulting continuous illumination of the lamp **511** and continuous operation of the signal device **535** indicate to the operator that the connection has been cleared out at one end thereof and is no longer desired.

The supervisory lamp **511** and signal device **535** are also energized when the connection extending to the called substation **T₅** is cleared out at this substation. Thus, it is pointed out above that, when the called party at the substation **T₅** restores his receiver to its hook, the hook switch arm **3457** is moved out of engagement with the associated switch spring **3456** to open the previously traced circuit by way of which the relays **R3470** and **R3110** and the impedance element **3216** are being held energized in series. The two relays **R3470** and **R3110** restore when this series circuit is interrupted, the last-mentioned relay operating to reverse battery back over the trunk line **61** extending to the repeater illustrated in Figs. 26 and 27. This repeater responds to the battery reversal in the manner previously described by causing a pulse of alternating current to be transmitted by way of the trunk line **37** to the repeater illustrated in Figs. 17 and 18. The control apparatus embodied in the last-mentioned repeater responds to the pulse of alternating current by reversing battery back over the line conductors of the operated incoming connector switch illustrated in Figs. 12 and 13, thereby to reverse the direction of current flow through the upper winding of the relay **R790**. The two windings of the relay **R790** are differentially energized and the relay restores to recomplete, at **RA791**, the previously traced circuit extending by way of the switch springs **759** for energizing the supervisory lamp **511** in series with the relay **R530**. The resulting continuous illumination of the lamp **511** and the continuous operation of the signal device **535** serve to signal the operator that the connection may be released.

As indicated above, the release of the finder-connector link illustrated in Figs. 19 and 20 is accomplished without the intervention of the operator in the exchange **B**. More particularly, when the relay **R685** restores in response to the release of the connection at the calling substation **T₁**, it interrupts at **RA687**, the operating circuit for the slow-acting relay **R690**, which latter relay, upon restoring, interrupts, at **RA692**, the operating circuit for the relay **R695** and opens, at **RA691**, a point in the path, traced previously by way of which ground potential is impressed upon the control conductor **C851** of the trunk line **36**. The removal of ground potential from this control conductor results in the deenergization of the two operated relays **R2040** and **R2050**, causing both of these relays to restore. The relay **R2040**, upon restoring, completes, at **RA2045**, the previously traced circuit for energizing the release magnet **2033** whereby the wipers of the Strowger switching mechanism **1900** are returned to rotary and vertical normal in the usual manner. At this time, the off-normal springs **2034** are opened to interrupt the operating circuit for the release magnet **2033**.

Also, the off-normal spring **2016** is moved from engagement with the associated spring **2017** and into engagement with the associated spring **2016'**, thereby to mark the link illustrated in Figs. 19 and 20 as idle in the bank contacts of the distributor switch **2200**. Thus, the finder-connector link illustrated in Figs. 19 and 20 is completely released and is available for use in completing another connection.

When ground potential is removed from the control conductor **C851** of the trunk line **36** in the manner just described, the line circuit associated with the calling line **34** is released in the manner explained previously. Thus, when ground potential is removed from the control conductor **C851**, the cut-off and lockout relays **R2120** and **R2130**, respectively, are caused to restore in the order named. The relay **R2120**, upon restoring, opens, at **RA2122**, the holding circuit for **R2160**, causing the last-mentioned relay to restore. Thus, all of the relays embodied in the line circuit associated with the calling line **34** are restored to normal and the line is marked as idle in the bank contacts of the numerical switches having access thereto.

When the operator in the exchange **B** receives the disconnect signal in the manner just explained, she may release the link line **552** and initiate the release of the operated switch train extending to the called substation **T₅** by restoring the two key switches **658** and **757** to normal. When the switch **757** is returned to its normal position, the springs **761** are opened to interrupt the operating circuit for the relay **R795** and the springs **760** are opened to interrupt the circuit for energizing the busy lamp **763**. Upon restoring, the relay **R795** interrupts, at **RA796**, the circuit for energizing the lower winding of **R790** and opens, at **RA797**, a point in the loop circuit by way of which the upper winding of **R790** is being held energized in series with the two windings of the line relay **R1705** embodied in the repeater illustrated in Figs. 17 and 18. At the time this loop circuit is interrupted, only the three relays **R1700**, **R1705** and **R1730** of the indicated repeater are operated. The relay **R1705**, upon restoring, opens at **RA1706** the operating circuit for the hold relay **R1700**. When the relay **R1700** restores, it opens, at **RA1703**, a point in the previously traced operating circuit for **R1730**. At **RA1701**, the relay **R1700**, upon restoring, opens one path and completes an alternative path for impressing ground potential upon the control conductor **C1379** of the trunk line **32** incoming to the repeater, this alternative path extending from ground at **RA1732** and by way of **RA1701** to the control conductor **C1379**. At **RA1706** and **RA1707**, respectively, the line relay **R1705**, upon restoring, completes alternative operating circuits for the two relays **R1840** and **R1820**; the circuit for energizing **R1840** extending from ground at **RA1706** by way of **RA1735**, **C1781** and the winding of **R1840** to battery; and the circuit for energizing **R1820** extending from ground at **RA1707** by way of **RA1737**, **C1784** and the winding of **R1820** to battery. Upon operating, the relay **R1840** connects the line conductors **C1885** and **C1886** of the trunk line **37** to opposite terminals of the alternating current source provided in the exchange **B**. The relay **R1820**, upon operating, disconnects the line terminals of the transformer windings **1878** and **1879** from the two line conductors of the trunk line **37**, in the manner explained previously. When the relay **R1700** restores, it completes, at **RA1702**, a circuit for energizing the

upper winding of R1830, this circuit extending from ground by way of RA1702, RA1734, C1779 and the upper winding of R1830 to battery. The relay R1830 now operates to prepare, at RA1831, a circuit for energizing the operating magnet 1772 of the minor switch 1770 and a holding circuit for itself. At RA1833, the relay R1830 prepares a circuit for energizing the slow-to-operate relay R1805. At RA1832, the relay R1830 completes a circuit extending by way of RA1812 for energizing the slow-acting relay R1800. The relay R1800, upon operating, completes at RA1801 the above-mentioned holding circuit for R1830, which circuit extends from ground at RA1831 by way of RA1801 and the upper winding of R1830 to battery. At RA1804, the relay R1800 completes the above-mentioned circuit for energizing the relay R1805, and the latter relay, upon operating, completes, at RA1807, an obvious circuit for energizing R1810. The relay R1805 also completes, at RA1806, an obvious multiple holding circuit for the relay R1830. When the relay R1810 operates, it opens, at RA1812, the operating circuit for R1800, thereby to initiate the sequential restoration of the three relays R1800, R1805 and R1810 in the order named. When the relay R1810 restores, it again completes, at RA1812, the operating circuit for R1800 whereby the three enumerated relays are caused again sequentially to operate. The cyclic operation of the three relays R1800, R1805 and R1810 continues until the relay R1830 is deenergized and restores. During the period of each cycle of operation of the three enumerated relays when the relay R1810 is energized, the above-mentioned circuit is completed for energizing the operating magnet 1772 of the minor switch 1770, this circuit extending from ground at RA1831 by way of RA1811, C1797 and the winding of the magnet 1772 to battery. Obviously, this circuit is also interrupted once during each operating cycle of the three cyclically operating relays. Each time the operating magnet 1772 is energized, it cooperates with its associated ratchet and pawl mechanism to step the wiper 1771 one step. When the wiper 1771 is moved to its first off-normal position, the off-normal springs 1774 are closed to prepare a circuit for energizing the release magnet 1773. Operation of the switch 1770 continues until the wiper 1771 is operated to its fifth off-normal position, at which time a path is completed for short-circuiting the winding of R1730. The path for short-circuiting the winding of the relay R1730 may be traced as extending from ground at RA1733 by way of the respective fifth contacts of the two contact sets embodied in the switch 1770 and the bridging wiper 1771 extending therebetween, the winding of R1730 and RA1738 back to ground at RA1757. When this short-circuiting path is completed, the relay R1730 is deenergized and restores to open, at RA1734, RA1735 and RA1737, the above-traced alternative operating circuits for the relays R1830, R1840 and R1820. The relay R1840 now restores to terminate the relatively long pulse of alternating current transmitted by way of the trunk line 37 to the repeater illustrated in Figs. 26 and 27. In cooperation with the relay R1820, the relay R1840 also functions to reconnect the line conductors C1885 and C1886 of the trunk line 37 to the line terminals of the two repeating transformer windings 1878 and 1879. When, shortly following the interruption of the operating circuit for R1830, the two relays R1800 and R1805 restore, the holding circuit for R1830 is opened, permitting the last-mentioned

relay to restore to open points in the respective operating circuits for R1800 and R1805. Thus, the cyclic operation of the three relays R1800, R1805 and R1810 is arrested. Upon restoring, the relay R1830 also completes, at RA1831, the above-mentioned circuit for energizing the release magnet 1773 of the minor switch 1770, which circuit may be traced as extending from ground at RA1831 by way of C1780, the closed off-normal springs 1774 and the winding of the release magnet 1773 to battery. The resulting operation of the release magnet 1773 causes the wiper 1771 of the switch 1770 to be returned to rotary normal in the usual manner, at which time the springs 1774 are opened to interrupt the operating circuit for the release magnet 1773. The relay R1730, upon restoring, not only initiates the restoration of the six relays R1800, R1805, R1810, R1820, R1830 and R1840 in the manner just described, but, in addition, opens at RA1738 a further point in its own holding circuit, interrupts, at RA1731 and RA1739, two additional points in the calling loop circuit, and initiates the release of the preceding operated incoming connector switch illustrated in Figs. 12 and 13. More particularly, the relay R1730, upon restoring, opens, at RA1733, the above-traced alternative path for impressing ground potential upon the control conductor C1379 of the trunk line 32 incoming to the repeater illustrated in Figs. 17 and 18. When ground potential is removed from this control conductor, the switching-through relay R1200 is deenergized and restores. The relay R1200, upon restoring, completes, at RA1205, a circuit for energizing the release magnet 1208, this circuit extending from ground by way of the resistor 1238, RA1244, RA1205, the off-normal springs 1207 and the winding of the magnet 1208 to battery. The resulting operation of the release magnet 1208 causes the wiper carriage structure embodied in the Strowger switching mechanism 1370 to be returned to normal in the usual manner, at which time the off-normal springs 1207 are opened to interrupt the operating circuit for the release magnet. Following the operation of this magnet and the return of the wiper carriage structure to normal, the incoming connector switch illustrated in Figs. 12 and 13 and the repeater shown in Figs. 17 and 18 are fully released.

When the release pulse of alternating current is transmitted by way of the trunk line 37 from the repeater illustrated in Figs. 17 and 18 to the repeater illustrated in Figs. 26 and 27 in the manner just explained, the relay R2650 is energized and operates to open, at RA2652 and its associated resting contact, a point in the previously traced holding circuit for R2605. At RA2652 and its associated working contact, the relay R2650 completes the previously traced circuit for energizing the lower winding of R2600 and the winding of R2705 in parallel. Since the duration of the release pulse is quite long, the relay R2650 is held operated for a time interval exceeding the period required for the slow-to-release relay R2605 to restore. Upon restoring, the relay R2605 completes the previously traced circuit for energizing the lower winding of R2660. When the relay R2640 operates, it performs the functions described previously; that is, it prepares the previously traced operating circuits for the relay R2660 and the rotary switch operating magnet 2787, and completes the operating circuit for the slow-acting relay R2670. Thus, the cyclic operation of the three relays R2670, R2660 and R2655 is again initiated. During each cycle of operation of these

relays, the previously traced operating circuit for the rotary magnet 2787 is completed. Thus, the wiper 2786 is driven over the contacts of its associated contact field at the rate of one step for each operating cycle of the three relays R2655, R2660 and R2670. When the wiper 2786 is moved into engagement with its respective associated third contacts, a circuit is completed for energizing the slow-to-release relay R2720, this circuit extending from ground at RA2652 by way of C2689, RA2738, RA2716, C2688, RA2614, C2687, the wiper 2788 bridging the third contacts of the bank contact field embodied in the minor switch 2785, and the winding of R2720 to battery. When energized over this circuit, the relay R2720 operates to open, at RA2722 and RC2723, the originally completed holding circuit for the relay R2710 and to complete a circuit for holding the relays R2710 and R2720 energized until the release pulse being transmitted by way of the trunk line 37 is terminated. The last-mentioned circuit extends from ground at RA2652 by way of C2689, RA2738 and RA2716 to RA2724 where it divides, one branch extending through the winding of R2720 to battery and the other branch extending by way of RA2721, RA2722 and the windings of R2710 to battery. Following the operation of the relay R2720, the relay R2710 is held energized until the alternating current release pulse being transmitted by way of the trunk line 37 is terminated. When the release pulse is terminated, the circuit just traced is interrupted at RA2752. The relay R2710 restores immediately this circuit is interrupted, but the relay R2720, due to its slow-to-release characteristic, remains operated for a short time interval thereafter. Upon restoring, the relay R2710 opens, at RA2714, a point in its original holding circuit and interrupts, at RA2711, RA2715 and RA2719, three points in the loop circuit extending from the line terminals of the repeating transformer 2615 to the operated incoming connector switch illustrated in Figs. 31 and 32. At RA2718, the relay R2710, upon restoring, opens a point in the holding circuit for R2620, causing the last-mentioned relay to restore. At RA2716, the relay R2710 opens a point in the operating circuit for the two relays R2600 and R2705, causing both of these relays to restore. When the relay R2620 falls back, it opens, at RA2625, a point in the above-traced operating circuit for the relay R2640. The holding circuit for the relay R2640 is opened during the period of the next cycle of operation of the three relays R2655, R2660 and R2670, when the two relays R2660 and R2670 are restored. Upon restoring, the relay R2640 opens points in the respective operating circuits for the two relays R2660 and R2670 and the operating magnet 2787, thereby to terminate the operation of the minor switch 2785 and the cyclic operation of the three relays R2670, R2660 and R2655. At RA2641, the relay R2640, upon restoring, completes the previously traced operating circuit for the release magnet 2788. The resulting operation of the magnet 2788 causes the wiper 2786 of the minor switch 2785 to be returned to its normal position in the usual manner. When this wiper reaches its home position, the off-normal springs 2789 are opened to interrupt the operating circuit for the release magnet 2788. Following the release of the minor switch 2785 in the manner just explained, the repeater illustrated in Figs. 26 and 27 is fully released.

The release of the incoming connector switch illustrated in Figs. 31 and 32 is initiated when the relay R2710 of the repeater illustrated in

Figs. 26 and 27 restores. More particularly, when this relay restores to open the loop circuit extending to the indicated incoming connector switch, the line relay R3125 restores to interrupt, at RA3126, the operating circuit for the slow-acting hold relay R3130. The hold relay R3130, upon restoring, opens, at RA3132, the operating circuit for the relay R3140, which latter relay, upon falling back, opens, at RA3141, a point in the common portion of the respective holding circuits for the relays R3150, R3155, R3200, R3235 and R3240, causing any operated ones of these relays to restore. At RA3143, the relay R3140 completes a path for applying ground to the conductor C3191, which conductor is multiplied to certain of the contacts of the contact set 3276 embodied in the bank contact field of the rotary switch 3250. This path may be traced as extending from ground at RA3103 by way of RA3126 and RA3143 to C3191. When this path is completed, the contacts numbered from one to twenty-four of the contact set 3276 are grounded, thereby to prepare a release circuit for causing the rotary magnet 3251 to return the wipers of the switch 3250 to normal. At RA3144, the relay R3140, upon restoring, completes an alternative circuit for energizing the lower winding of R3150 in series with the winding of R3155, this alternative circuit extending by way of the grounded test wiper 3255, C3195, RA3171, RA3144, RA3104, the lower winding of R3150 and the winding of R3155 to battery. When its lower winding is energized over the circuit just traced, the relay R3150 partially operates to close the "X" contacts associated with RA3152 but such operation is without effect at this time. The relay R3155, on the other hand, fully operates to complete, at RA3159 and RA3158, a holding circuit for itself, which circuit extends by way of the grounded wiper 3255, C3195, RA3159, RA3158, the lower winding of R3150 and the winding of R3155 to battery. The relay R3155, upon operating, also completes the above-mentioned release circuit for energizing the operating magnet 3251 of the rotary switch 3250. The last-mentioned circuit extends by way of the grounded test wiper 3255, C3195, RA3159, RA3158, RA3104, RA3144, RA3151, C3194, the armature 3258 and the winding of the magnet 3251 to battery. Due to the circuit interrupting action of the contact springs associated with the armature 3258 and, further, to the fact that ground potential is present upon all of the contacts of the contact set 3276 other than the twenty-fifth contact, the operating magnet 3251 operates in a buzzer-like manner to drive the wipers of the switch 3250 until they are moved into engagement with their respective associated twenty-fifth contacts which constitute the home position of the switch. When the wipers of the switch 3250 are driven to the home position, the test wiper 3255 is disconnected from ground to interrupt the release circuit with the result that the operation of the switch 3250 is arrested. Also, when ground potential is removed from the wiper 3255, the relays R3150 and R3155 are de-energized and restore. Following the restoration of the relay R3155, all of the relay equipment embodied in the incoming connector switch illustrated in Figs. 31 and 32 is released and this switch is prepared for use in connection with another call.

The release of the line circuit illustrated in Fig. 34 and associated with the called line 60 is initiated when the relay R3140 restores. Thus,

when the relay R3140 falls back, it opens, at RA3141, a point in the path, traced previously, by way of which ground potential is impressed upon the control conductor C3482 of the line 60. The removal of ground potential from the control conductor C3482 results in the deenergization of the cut-off relay R3440 embodied in the line circuit associated with the called line 60. When the cut-off relay R3440 restores, it 10 interrupts, at RA3445, the operating circuit for the slow-acting lockout relay R3430. The last-mentioned relay restores, after an interval, to reprepare, at RA3432, the start circuit extending to the distributor illustrated in Fig. 30 associated with the switching selector repeaters located in the exchange C. Following the release of the lockout relay R3430, the line circuit associated with the called line 60 is restored to normal. Thus, the connection between the calling and called substations T₁ and T₅ is fully 20 released.

SUBSECTION E.—Extension of the connection by way of the exchange C to a substation line terminating at the exchange D when the operator in the exchange B is on duty

As indicated previously, a call originating at a substation associated with a line terminating at the exchange B and intended for a substation associated with a line extending to the exchange D is normally routed to the operator's position in the exchange A and from this exchange through the automatic switching apparatus in the exchange D to the desired substation line terminating at the exchange D. In special or emergency cases such a connection may be routed from the operator's position in the exchange B through the automatic switching apparatus provided in the exchanges B, C and D to the desired substation line without the intervention as an operator located in the exchange A. Thus, if the operator in the exchange B, upon answering the call forwarded to her position from the calling substation T₁ in the manner explained in this section—Subsection A, is informed by the calling subscriber that the desired substation is associated with a line terminating at the exchange D, she may cause the desired connection to be set up by seizing the incoming connector switch illustrated in Figs. 12 and 13 and thereafter dialing the appropriate line selecting digits. The connection is progressively forwarded through the indicated incoming connector switch, over one of the trunk lines in the group including the trunk line 37, through the repeaters associated with the respective ends of the selected trunk line, through the incoming connector switch located in the exchange C and associated with the selected trunk line, over the trunk line 65, through the repeaters 57 and 66, and through the incoming connector switch 69 to the desired called substation line extending to the last-mentioned exchange as successive digits of the directory number designating the called substation are dialed. More particularly, the connection may be forwarded by way of the incoming connector switch illustrated in Figs. 12 and 13, over the trunk line 32, through the repeater illustrated in Figs. 17 and 18, over the trunk line 37 and through the repeater illustrated in Figs. 26 and 27 to the incoming connector switch illustrated in Figs. 31 and 32 in the exact manner described in the preceding subsection with reference to the call forwarded to the substation T₅. In the present case, however, since it is necessary 75

to transmit the impulses of two or more digits to the incoming connector switch 69 located in the exchange D, it is also necessary that the incoming connector switch, illustrated in Figs. 31 and 32, operate to switch the loop circuit through to the repeater 57 which terminates one end of the trunk line 65 extending to the exchange D in order that this repeater may respond to the impulses of the final digits dialed and relay the impulses to the switching equipment located in the distance exchange D. With the arrangement illustrated, only the single trunk line 65 is provided for interconnecting the exchanges C and D. This trunk line extends between the repeater 66 located in the exchange D and the repeater 57 located in the exchange C, both of which repeaters are identical in arrangement with the repeater illustrated in Figs. 26 and 27. The incoming connector switches provided in the exchange C have access to the repeater 57 over the trunk line 64, which trunk line includes two line conductors and a control conductor terminating at the respective first contacts of the contact sets 3271, 3274 and 3277 embodied in the bank contact field of the rotary switch 3250.

After the connection has been routed from the operator's position in the exchange B to the incoming connector switch illustrated in Figs. 31 and 32, in the manner explained previously, and the last-mentioned switch is seized, a single digit of one impulse must be transmitted thereto in order to cause the switch to select the trunk line 64 extending to the repeater 57. The manner in which this switch responds to the one impulse of the trunk selecting digit is identical with its mode of operation as explained in the immediately preceding subsection. At the end of the digit, the wipers 3251 to 3256, inclusive, of the rotary switch 3250 are left standing in engagement with their respective associated first contacts so that the test circuit including the lower winding of the busy test relay R3200 is completed. If the trunk line 64 is engaged in another call at the time it is selected by the incoming connector switch, the incoming connector switch operates to cause busy tone to be returned to the operator in the exchange B in the exact manner described in the preceding subsection. On the other hand, if the trunk line 64 is idle at the time it is selected, the line switching relay R3240 is caused to operate in the manner explained previously. Upon operating, the relay R3240 completes, at RA3244 and RA3245, its holding circuit as traced above. At RA3246, the relay R3240 opens a point in the circuit for energizing the rotary switch operating magnet 3257, thereby to prevent further impulses dialed at the calling operator's position from causing further operation of the rotary switch. At RA3243, the relay R3240 completes a circuit for energizing the switching-through relay R3100, this circuit extending from ground at the first contact of the contact set 3273 by way of the wiper 3252, RA3243, C3178 and the winding of R3100 to battery. 65 When energized over this circuit, the relay R3100 operates to complete, at RA3101 and RA3106 and their respective associated working contacts, an uninterrupted metallic loop circuit extending from the repeater illustrated in Figs. 26 and 27 through the incoming connector switch illustrated in Figs. 31 and 32 and over the line conductors of the trunk line 64 to the repeater 57, thereby to cause the seizure of the repeater 57 in the manner explained in detail previously with reference to the corresponding repeater illus-

trated in Figs. 17 and 18. The loop circuit which is completed in response to the operation of the relay R3100 may be partially traced as extending from the negative line conductor of the trunk line 64 by way of the wiper 3251, RA3241, C3175, 5 RA3101, C2890, RA2711, C2675, the repeating transformer winding 2618, RA2613, C2686, RA2715, the lower winding of R2700, the resistor 2701', the transformer winding 2619, C2695, 10 RA2719, C2891, RA3106, C3199, RA3248, the wiper 3256 and the first contact of the contact set 3271 to the opposite positive line conductor of the trunk line 64.

When the alternating current repeater 57 is seized through the completion of the loop circuit just described, it operates to return ground potential over the control conductor of the trunk line 64, thereby to complete a holding circuit for the relay R3240, which holding circuit may be traced as extending by way of the grounded control conductor of the trunk line 64, the wiper 3253, RA3244, RA3245 and the upper winding of R3240 to battery. The repeater 57 also functions, in the manner explained previously with reference to the corresponding repeater illustrated in Figs. 17 and 18, to transmit a seizing pulse of alternating current by way of the trunk line 65 to the repeater 66 located in the distant exchange D. The last-mentioned repeater responds to the seizing pulse, in the manner explained previously with reference to the similar repeater illustrated in Figs. 26 and 27, by completing a loop circuit to the incoming connector switch 69, whereby this incoming connector switch is seized and conditioned to respond to the impulses relayed thereto through the repeater chain comprising the repeater illustrated in Figs. 17 and 18, the repeater 57, and the repeater 66.

To continue with the operation of the incoming connector switch illustrated in Figs. 31 and 32, when the relay R3100 operates, it opens, at RA3102 and RA3105 and their respective associated resting contacts, two points in the operating circuit for the line relay R3125. At RA3102 and its associated working contact, the relay R3100 completes a new circuit for energizing the line relay R3125, which circuit extends from ground at the lower terminal of the lower winding of R3125 by way of this winding, the lower winding of R3120, RC3116, RA3115, the resistor 3108, RA3102, RA3112, RC3113, the upper winding of R3120 and the upper winding of R3125 to battery. Due to the relatively high resistance of the resistor 3105, the current traversing the circuit just traced is insufficient to maintain the line relay R3125 operated but is of sufficient magnitude to delay the release of the line relay R3125 for a substantial time interval. At RA3103, the relay R3100 opens a point in the operating circuit for the relay R3130, thereby to cause the sequential restoration of R3130 and R3140. At RA3103, the relay R3100 also opens a point in the circuit, traced previously, for energizing the rotary switch operating magnet 3257. At RA3104, the relay R3100 opens a point in the previously traced alternative operating circuit for the relay R3155. When the relay R3140 falls back, it opens, at RA3141, a point in the common portion of the respective holding circuits for the two relays R3150 and R3155, whereby both of these relays are caused to restore. Following the restoration of the relays R3125, R3130, R3140 and R3150, no further relay operations occur in 75

the incoming connector switch illustrated in Figs. 31 and 32 until the connection is released.

As indicated above, the impulses of the final two or three line selecting digits dialed at the operator's position in the exchange B are relayed through the operated repeater chain to the incoming connector switch 69 located in the distant exchange D. This incoming connector switch is of identical arrangement with that shown in Figs. 31 and 32 and responds to the impulses transmitted thereto by selecting the desired called subscriber's line as for example the line 74 extending to the called substation T₇. In this case, as in the case of the incoming connector switch illustrated in Figs. 31 and 32, the operation of the incoming connector switch 69 is different depending upon the character of the line being called. Thus, if the called line is of the single party or duplex type, such, for example, as the line 74, only two series of impulses are transmitted to the incoming connector switch 69. On the other hand, if the called line is of the multiplex type, three series of impulses are transmitted to the switch 69, the third series of impulses being repeated by the switch 69 to the line selecting apparatus individually associated with the selected subscriber's line. After the called line is selected, it is tested to determine the idle or busy condition thereof. If the line is occupied with another call, busy tone is returned over the connection to the operator's position in the exchange B. After receiving busy tone, the operator may cause a toll offering connection to be established to the busy called line in a manner which will be clearly apparent in view of the general description appearing in Section I and the detailed description appearing in the immediately preceding subsection of the specification. If the selected line is found to be idle, ringing current is projected over the called line to signal the called substation. Assuming that the called line is idle, the incoming connector switch 69 operates to reverse battery over the trunk line extending to the repeater 66 when the call is answered at the called substation. This repeater responds to the battery reversal by operating to transmit a supervisory pulse of alternating current over the trunk line 65 to the alternating current repeater 57. The last-mentioned repeater, in turn, responds to the supervisory pulse of alternating current by reversing battery back over the trunk line 64 and through the incoming connector switch shown in Figs. 31 and 32 to the repeater shown in Figs. 26 and 27. When battery is reversed over the line conductors of the trunk line 61, the repeater shown in Figs. 26 and 27 operates to transmit a supervisory pulse of alternating current by way of the trunk line 37 to the repeater shown in Figs. 17 and 18, causing the last-mentioned repeater to reverse battery over the trunk line 32 and through the incoming connector switch shown in Figs. 12 and 13 and thus cause the operation of the supervisory relay R190 embodied in the operator's position equipment located in the exchange B. When this relay operates the supervisory lamp 511 is deenergized and the operation of the signal device 535 is arrested so that the operator is informed that the desired connection is fully established.

If, after the connection is fully established to the called substation T₇, the called party desires to resignal the operator in the distant exchange B, he may do so by operating the hook switch provided at the called substation up and down,

in the usual manner, one or more times, thereby momentarily to interrupt the loop circuit extending from the incoming connector switch 69 to the called substation. The four repeaters 66, 57, 50 and 24 respond to the momentary interruptions of the loop circuit extending to the called substation, in the manner explained in the preceding subsection, to cause the restoration and operation of the supervisory relay R790. Thus, each time the indicated loop circuit is opened and closed, the four enumerated repeaters cooperate to cause the momentary restoration of R790, which relay, upon restoring, completes the circuit for energizing the signal lamp 511 and the relay R530, whereby the lamp 511 is energized and operation of the signal device 535 is initiated. At the end of the conversation and when the connection is cleared out at the called substation T₇, the four enumerated repeaters again cooperate to cause the restoration of the relay R790. At this time, the indicated relay remains in its restored position so that the lamp 511 is continuously energized and the signal device 535 continuously operates, whereby a disconnect signal is given to the operator in the exchange B. The same disconnect signal is given to the operator, in the manner explained previously, when the connection is cleared out at the calling substation T₁. Also, the operated switch train by way of which the connection is routed from the calling substation T₁ to the operator's position in the exchange B is released in the exact manner set forth in the preceding subsection. The repeater illustrated in Figs. 17 and 18, the repeater illustrated in Figs. 26 and 27, and the incoming connector switch illustrated in Figs. 12 and 13 are released in the manner previously explained when the operator in the exchange B clears out the connection. During the release of the repeater 50 illustrated in Figs. 26 and 27 and when the relay R2710 restores, the previously traced loop circuit extending through the incoming connector switch of Figs. 31 and 32 to the repeater 57 is interrupted. When this loop circuit is opened, the repeater 57 is released, in the manner explained in the preceding subsection with reference to the repeater shown in Figs. 17 and 18. During the release of this repeater, a relatively long release pulse of alternating current is transmitted by way of the trunk line 65 to the repeater 66. During its release, the repeater 57 also removes ground potential from the control conductor of the trunk line 64, thereby to deenergize the line switching relay R3240. When the last-mentioned relay restores, it opens, at RA3243, the operating circuit for the switching-through relay R3100, which latter relay, upon restoring, completes at RA3103, and RA3104, the previously-traced circuit for energizing the lower winding of R3150 in series with the winding of R3155. When the relay R3155 operates it completes the previously traced circuit for energizing the rotary switch operating magnet 3257 by way of the circuit interrupting contacts associated with the armature 3258. Thus, the rotary switch 3250 is caused to operate buzzer fashion to return the wipers 3250 to 3256, inclusive, to their respective home positions, at which time the relays R3150 and R3155 are deenergized and restore and the operating circuit for the magnet 3257 is opened. Thus, the incoming connector switch illustrated in Figs. 31 and 32 is fully released. When the alternating current release pulse is transmitted from the repeater 57 over the trunk line 65 to the repeater 66, the last-

mentioned repeater is released, in the manner explained in the preceding subsection with reference to the similar repeater shown in Figs. 26 and 27. During the release of the repeater 66, 5 the loop circuit extending to the operated incoming connector switch 69 is opened and this incoming connector switch is restored to normal in the manner explained previously with reference to the corresponding incoming connector switch of Figs. 31 and 32. Thus, the connection from the operator's position in the exchange B to the desired called substation is completely released. 10

SUBSECTION F.—Extension of the connection by way exchanges B, C and D to the operator's position 10 in the exchange A

As indicated in Section 1 of the specification, 15 the connection as routed to the operator's position in the exchange B may be extended by way of the automatic switching apparatus in the exchanges B, C and D, respectively, and the trunk line 13 to the operator's position 10 in the exchange A. Normally, this method of routing the 20 connection from the exchange B to the exchange A is not necessary, since one of the trunk lines in the group including the line 12 may be utilized for forwarding the connection from the exchange B directly to the exchange A. In cases of emergency, however, when the trunk lines of the group 25 including the line 12 may be out of service, the alternative routing of calls through the exchanges C and D to the exchange A may be necessary. The manner in which the connection is forwarded 30 from the operator's position in the exchange B, through the switching equipment in the exchange C, over the trunk line 65 and through the alternating current repeater 66 to the incoming connector switch 69 is exactly the same as described 35 in the preceding sub-section of this section. Following seizure of the incoming connector switch 40 69, a single digit of one impulse is dialed at the operator's position in the exchange B, this impulse being repeated through the repeater chain 45 comprising the repeaters 24, 50, 57 and 66 to the incoming connector switch 69 to cause the wipers of this switch to be operated into engagement with the contacts terminating the trunk line extending to the repeater 72. Thus, the repeater 50 72 is seized and a loop circuit is completed between this repeater and the repeater 66. When the repeater 72 is seized by the incoming connector switch 69, it operates to transmit a seizing pulse of alternating current by way of the trunk line 13 to the equipment 10_b provided at the operator's position 10 in the exchange A. The equipment 10_b provided at this position is in all respects identical with the equipment 10_a and shown in Fig. 4, the operation of which is explained in this section—Subsection C. More particularly, the equipment 10_b provided at the operator's position 10 responds to the seizing pulse of alternating current transmitted by way of the trunk line 13 by causing the line signal lamp 66 embodied in the apparatus 10_b to be illuminated to signal the operator that an incoming call awaits attention. When the operator at the position 10 answers the call by inserting her line connecting and answer plug in the answer jack 70 included in the apparatus 10_b, this apparatus operates to cause a supervisory pulse of alternating current to be transmitted back over the trunk line 13 to the alternating current repeater 72. The last-mentioned repeater responds to the 75 supervisory pulse of alternating current by re-

versing battery back through the incoming connector switch 69 to the repeater 66, which latter repeater responds, in the manner explained above, to cause a supervisory pulse of alternating current to be transmitted by way of the trunk line 65 to the alternating current repeater 57. The repeater 57, in turn, reverses battery back over the trunk line 64 and through the incoming connector switch 53 to the alternating current repeater 50 illustrated in Figs. 26 and 27. The repeater 50 responds to the reversal of battery there-to by transmitting a supervisory pulse of alternating current over the trunk line 37 to the repeater 24 located in the exchange B and illustrated in Figs. 17 and 18. Finally, the repeater 24 responds to the last-mentioned supervisory pulse of alternating current by reversing battery through the incoming connector switch of Figs. 12 and 13 to the apparatus provided at the operator's position in the exchange B, whereby the relay R790 is caused to operate to open the circuit for energizing the signal lamp 511. Thus, when the call is answered at the operator's position 10, the supervisory lamp 511 is deenergized to indicate to the operator in the exchange B that the call has been answered. After the connection has been routed to the operator's position 10 in the exchange A, it may be extended to the desired called substation in the manner conventionally followed in manual office practice.

The release of the operated switch train by way of which the connection is set up between the operator's position in the exchange B and the operator's position in the exchange A is partially under the control of the operator in the exchange B and partially under the control of the operator at the position 10 in the exchange A. Thus, when the operator in the exchange B clears out the connection by restoring the connect keys to normal, the incoming connector switch illustrated in Figs. 12 and 13, the repeater 24 illustrated in Figs. 17 and 18, the repeater 50 shown in Figs. 26 and 27, the incoming connector switch 53 shown in Figs. 31 and 32, the repeater 57, and the repeater 66 are all released in the manner explained in the preceding subsection. The equipment provided at the operator's position 10, the alternating current repeater 72 and the incoming connector switch 69, on the other hand, are only released when the operator at the position 10 in the exchange A withdraws her line connecting plug from the answer jack embodied in the apparatus 10_b. When this operation is performed, the apparatus 10_b and the alternating current repeater 72 are released in the exact manner described in this section—Subsection C with reference to the apparatus 10_a, shown in Fig. 4 and the repeater illustrated in Figs. 10 and 11. During the release of the repeater 72, ground potential is removed from the control conductor embodied in the trunk line extending from the incoming connector switch 69 to the repeater 72, so that the operated relays in this connector switch and corresponding to the relays R3100 and R3240 of the incoming connector switch 53 are caused to restore to initiate the release of the connector switch 69 in the manner explained in this section—Subsection E.

SUBSECTION G.—Extension of the connection through the exchange A to a substation associated with a line terminating at exchange D

As pointed out in the preceding subsection, calls initiated at substations associated with lines terminating at the exchange B and intended

for substations associated with lines terminating at the exchange D are normally routed to an operator's position in the exchange A and are completed with the assistance of the operator in the exchange A who answers the call. For example, if the call initiated at the substation T₁ and forwarded to the operator's position in the exchange B is intended for the substation T₇ associated with the line 14 terminating at the exchange D, the operator who answers the call in the exchange B may forward the connection to an operator's position in the exchange A in the manner explained in this section—Subsection B, assuming that the call is routed to the exchange A over the trunk line 12 to the equipment 10, provided at the operator's position 10, the operator who answers the call may forward the connection to the desired called substation by utilizing the equipment 10_b which terminates the inter-office trunk line 13. More particularly, the connection may be forwarded from the answering operator's position in the exchange A to the desired called substation T₇ in the exchange D in the exact manner described in Section 9—Subsection D. The manner in which the incoming connector switch 67, by way of which the connection is routed to the called line 14, operates to select the called line and to perform the auxiliary functions incident to the completion of the connection is exactly the same as described previously in this section—Subsection C with reference to the corresponding incoming connector switch shown in Figs. 31 and 32.

SUBSECTION H.—Extension of the connection from the operator's position in the exchange B to a substation associated with a line terminating at the exchange F

If the call, as initiated at the substation T₁ and extended to the operator's position in the exchange B, is to be forwarded to a substation associated with a line extending to the exchange F, the operator in the exchange B may cause the desired connection to be set up by first operating the switch 707 embodied in the apparatus associated with the trunk line 42 to its off-normal position to seize the trunk line 42 and thereafter dialing the appropriate digits of the directory number designating the called substation. More particularly, when the switch 707 is operated to its off-normal position, the line terminals of the repeating transformer windings 716 and 717 are connected to the line conductors C547 and C548 of the link line 553 and the springs 711 are closed to complete an obvious circuit for energizing the relay R745 in parallel with the busy lamp 760. At the springs 709, a circuit, extending by way of C546, is completed for energizing the transmitter 500 in series with the transformer winding 505 and the retard coil 507. At the springs 710, a circuit, traced hereinafter, is prepared for energizing the relay R730. The relay R745, upon operating, completes, at RA747, an obvious circuit for energizing the upper winding of the relay R740 and prepares, at RA746, a circuit, traced hereinafter, for energizing the supervisory lamp 511 in series with the winding of the relay R530. At RA748, the relay R745 connects the lower winding of R740 in series with the resistor 737 across the line conductors of the trunk line 42 extending to the exchange F, thereby to complete a loop circuit to the incoming connector switch provided in the exchange F and terminating the distant end of the trunk line 42. More particularly, this loop circuit may be par-

tially traced as extending by way of the upper conductor of the trunk line 42, the switch springs 824 and 825, C839, RA732, RC735, the transformer winding 719, the resistor 737, the lower winding of R740, RA748, the transformer winding 721, RC736, RA734, C840 and the switch springs 828 and 827 to the opposite line conductor of the trunk line 42. The resulting seizure of the incoming connector switch terminating the distant end of the trunk line 42 results in the conditioning of this switch to respond to the operation of the calling device 508 provided at the operator's position in the exchange B. The differentially wound relay R740 operates, when its lower winding is energized over the above-traced loop circuit and, upon operating, opens, at RA741, a point in the circuit for energizing the supervisory lamp 511 in series with the winding of the relay R530. As previously explained, during each back stroke of the dial embodied in the device 508, the shunt springs 509 are closed to complete the previously traced operating circuit for R540, which relay, upon operating, completes, at RA542, the previously mentioned circuit for energizing R730. This circuit may be traced as extending from ground by way of the shunt springs 509, RA542, C549, the switch springs 710 and the winding of R730 to battery. Upon operating, the relay R730 disconnects the line conductors C839 and C840 of the link line 833 from the line terminals of the repeating transformer windings 719 and 721 and connects the indicated line conductors to the pulsing springs 510 of the calling device 508. During the back stroke of the dial embodied in the calling device 508, the springs 510 are opened a number of times to interrupt the loop circuit extending to the seized incoming connector switch provided in the exchange F, the number of interruptions being determined by the particular digit dialed. At the end of each back stroke of the dial, the shunt springs 509 are opened to interrupt the operating circuit for the relay R540 and the above-traced operating circuit for the relay R730. The relay R730, upon restoring, disconnects the conductors of the link line 833 from the pulsing springs 510 and reconnects these conductors to the line terminals of the transformer windings 719 and 721. The operated incoming connector switch in the exchange F responds to the impulses of the first digit by selecting a particular group of lines including the called line, while the impulses of the second digit serve to cause the incoming connector switch to select the called line from the selected group of lines. If the desired substation is associated with a line of the multiplex type, a third series of impulses is transmitted by way of the trunk line 42 to the incoming connector switch in the exchange F, and the impulses of this series are repeated by the control apparatus provided in the operated incoming connector switch to the station selecting apparatus associated with the selected line. The arrangement of the operated incoming connector switch provided in the exchange F is similar to that of the switch illustrated in Figs. 31 and 32 and described previously in that it performs the usual functions of testing the called line to determine the idle or busy condition thereof, returning busy tone over the calling loop to signal the calling operator in the event the called line is busy, and projecting ringing current over the selected called line to energize the signal device at the called substation in the event the selected called line is idle at the time it is seized. 75

If the called line is busy, the operator may cause a toll offering connection to be established to the called line by operating the toll offering switch 753' to unbalance the loop circuit extending to the operated incoming connector switch provided in the exchange F. The manner in which this incoming connector switch operates to establish the toll offering connection is similar to the operation of the incoming connector switch of Figs. 31 and 32 to establish a similar type of connection. When the call is answered, the incoming connector switch provided in the exchange F functions to reverse battery back over the trunk line 42, thereby to reverse the direction of current flow through lower winding of the differentially wound relay R740. The two windings of this relay are now cumulatively energized so that the relay operates to open a point in the previously-mentioned circuit for energizing the supervisory lamp 511 in series with the winding of R530. In order to complete the desired conversational circuit between the calling and called substations, the operator in the exchange B may utilize one of the link lines, as, for example, the line 552, to establish a tie or jumper connection between the established talking circuits extending to the calling and called substations. If the link line 552 is used for this purpose, the two line connecting switches 658 and 701 are operated to the off-normal position so that the line terminals of the transformer windings 651 and 652 are connected by way of the conductors C688 and C689 to the line terminals of the two transformer windings 716 and 717. When the switch 701 is operated to its off-normal position, the springs 704 are closed to complete an obvious alternative circuit for maintaining the busy lamp 760 and the relay R745 energized. At the springs 703 a point is prepared in the above-mentioned circuit for energizing the supervisory lamp 511 in series with the winding of the relay R530. Following the completion of this tie connection and the answering of the call at the called substation, the desired talking circuit between the calling and called substations is fully established. After the tie connection described above is completed, the operator may restore the two call and answer switches 666 and 707 to normal so that the link line 553, extending to the operator's telephone equipment, is released. At the end of the conversation and when the connection is cleared out at either the calling or the called substation, the supervisory lamp 511 is illuminated to give the operator in the exchange B a disconnect signal. The manner in which this lamp is energized when the calling party at the substation T₁ hangs up is explained in this section—Subsection D. When the connection is cleared out at the called substation, the operated incoming connector switch provided in the exchange F again operates to reverse battery back over the trunk line 42, thereby to reverse the polarity of the current traversing the lower winding of R740. This relay is now differentially energized and restores to complete, at RA741, the above-mentioned circuit for energizing the signal lamp 511 in series with the winding of the relay R530, this circuit extending from ground at RA746 by way of RA741, the switch springs 703, C543, the filament of the lamp 511 and the winding of R530 to battery. The resulting continuous illumination of the lamp 511 indicates to the operator that the connection is no longer desired. As explained previously, if the key switch 513 occupies its off-normal position, the

visual signal provided by the lamp 511 is supplemented by the operation of the buzzer 535, which buzzer is energized in response to the operation of the relay R530.

The release of the switching equipment utilized in extending the connection from the calling substation T₁ to the operator's position in the exchange B is accomplished in the manner explained in this section—Subsection D. The release of the switch train, by way of which the connection is routed from the operator's position in the exchange B to the called substation in the exchange F, is under the control of the operator in the exchange B. More particularly, when the operator restores the switch 701 to normal, the springs 704 are opened to interrupt the parallel circuit for energizing the busy lamp 760 and the relay R745. Also, when the two key controlled switches 701 and 658 are restored to normal, the link line 552 is released for further use. When the relay R745 restores, it interrupts, at RA1747, the circuit for energizing the upper winding of R1740 and opens, at RA1748, a point in the loop circuit extending by way of the trunk line 42 to the operated incoming connector switch located in the exchange F. This incoming connector switch is released in response to the interruption of the loop circuit in the manner explained above with reference to the incoming connector switch shown in Figs. 31 and 32. Thus, the connection is entirely released.

SUBSECTION I.—Extension of the connection from the operator's position in the exchange B to a substation associated with a line terminating at the exchange E

If the call initiated at the substation T₁ and forwarded to the operator's position in the exchange B is to be extended to a substation, as, for example, the substation T₂, associated with a line terminating at the exchange E, the operator may cause the desired connection to be established by seizing the incoming connector switch illustrated in Figs. 12 and 13 in the manner explained in this section—Subsection D, and thereafter dialing the appropriate line selecting digits. The indicated incoming connector switch responds to the impulses of the first two digits dialed by the operator, in the manner set forth in Subsection D of this section, to select a trunk line extending to an idle repeater in the group including the repeater 20. If it be assumed, for example, that the line 31 is the first available idle trunk line in this group, the rotary movement of the wipers embodied in the switching mechanism 1370 is arrested when these wipers are positioned upon the contacts terminating the conductors of the trunk line 31. Following the selection of this line, the incoming connector switch of Figs. 12 and 13 operates to switch the calling loop circuit through to the repeater 20, thereby to energize the line relay R1655. One branch of the calling loop circuit may be partially traced as extending from ground at the lower terminal of the upper winding of R1655 by way of this winding, the upper winding of R1630, RC1629' and RA1629 to the trunk line conductor C1682, while the opposite branch of the loop circuit may be partially traced as extending from battery at the upper terminal of the lower winding of R1655 by way of this winding, the lower winding of R1630, RC1626 and RA1625 to the opposite trunk line conductor C1681. Upon operating, the relay R1655 completes, at RA1656, an obvious circuit for energizing the slow-acting

hold relay R1660 and prepares, at RA1657, a loop circuit extending to the incoming connector switch shown in Figs. 24 and 25 and located in the exchange E. The hold relay R1660, upon operating, completes, at RA1661, an obvious path for impressing ground potential upon the control conductors C1683 and C1686 of the trunk lines 31 and 38, respectively, thereby to maintain these trunk lines marked as busy in the bank contacts of the connector switches having access thereto and to prevent the release of the operated incoming connector switch illustrated in Figs. 12 and 13. At RA1662, the relay R1660 completes an obvious circuit for energizing the slow-to-release line switching relay R1665, causing the last-mentioned relay to operate and complete, at its armatures RA1666 and RA1667, the above-mentioned loop circuit extending by way of the trunk line 31 to the incoming connector switch of Figs. 24 and 25. At RA1662, the relay R1660 also completes an obvious circuit for energizing the polarizing winding of the electropolarized relay R1640, but the last-mentioned relay does not operate at this time. The loop circuit extending to the incoming connector switch of Figs. 24 and 25 may be traced as extending from ground at the lower terminal of the lower winding of R2420 by way of this winding, the lower winding of R2415, RA2414, RA2403, C2477, RA1667, RA1657, the transformer winding 1674, the left winding of R1640, the transformer winding 1673, RA1666, C2476, RA2401, RA2412, the upper winding of R2415 and the upper winding of R2420 to battery. Due to the direction of current flow through the left winding of the polarized relay R1640, this relay does not operate at this time. Also, the relay R2415, which is of the differentially wound type, does not operate when both of its windings are energized over the loop circuit just traced. The line relay R2420, however, operates to open, at RA2422, a point in the circuit, traced hereinafter, for energizing the two relays R2440 and R2450 and the operating magnet 2561 of the rotary switch 2550. At RA2423, the relay R2420 prepares a path, traced hereinafter, for impressing negative battery potential upon the positive line conductor of a selected called line. At RA2421 and its associated working contact, the relay R2420 completes an obvious circuit for energizing the slow-acting hold relay R2425, which latter relay now operates to open, at RA2426, one of the multiple paths for impressing ground potential upon the all-switch-busy conductor C2404 and to complete, at RA2427, an obvious circuit for energizing the relay R2430. The relay R2430, upon operating, opens, at RA2432 and its associated resting contact, a point in the circuit, traced hereinafter, for energizing the relay R2400 and completes, at RA2432 and its associated working contact, an obvious path for impressing ground potential upon the control conductor C2409, thereby to mark the incoming connector switch of Figs. 24 and 25 as busy in the contacts of the switching selector repeaters having access thereto. At RA2431, the relay R2430 prepares holding circuits for certain of the relays mentioned hereinafter and, at RA2433 and RA2434, it prepares points in the above-mentioned circuit for energizing the rotary switch operating magnet 2561 in parallel with the two relays R2440 and R2450. At RA2434', the relay R2430 opens a point in the circuit, traced hereinafter, for energizing the relay R2435. Following the operation of the relay R2430, the incoming connector switch illustrated in Figs. 24 and 25 and

provided in the exchange E is conditioned to respond to the third series of impulses dialed at the calling operator's position in the exchange B. During operation of the calling device provided at the operator's position, the calling loop circuit, which is now extended through to the repeater 20, is interrupted in the usual manner to cause the alternate restoration and operation of the line relay R1655. More particularly, this relay restores during the open circuit period of each impulse dialed at the calling substation and interrupts, at RA1657, the loop circuit extending to the operated incoming connector switch of Figs. 24 and 25. At RA1656, the relay R1650 opens the operating circuit for the hold relay R1660, but the last-mentioned relay, due to its slow-to-release characteristic, remains operated during impulsion.

Each time the loop circuit extending by way of the trunk line 31' to the incoming connector switch of Figs. 24 and 25 is interrupted, the line relay R2420 restores. When the relay R2420 restores at the beginning of the first impulse of the first series of impulses transmitted over the trunk line 31' to the incoming connector switch, it opens, at RA2421, the operating circuit for the hold relay R2425 and completes, at RA2421 and RA2422 and their associated resting contacts, the above-mentioned circuit for energizing the winding of R2440 in parallel with the lower winding of R2450 and the winding of the rotary switch operating magnet 2561. This circuit may be traced as extending from ground at RA2421 by way of RA2433 to RA2463, where it divides, one branch extending through the lower winding of R2450 to battery, a second branch extending through the winding of R2440 to battery, and the third branch extending by way of RA2422, RA2434, C2488, RA2536 and the winding of the magnet 2561 to battery. When energized over this circuit, the two relays R2440 and R2450 both operate. The operating magnet 2561 also operates to condition the associated ratchet and pawl mechanism to step the wipers of the rotary switch 2550 to their respective first off-normal positions. Upon operating, the relay R2440 completes, at RA2441, an obvious holding circuit for the relay R2450 and completes, at RA2442, an obvious path shunting the armature RA2463 of the busy test relay R2460. The relay R2450, upon operating, opens, at RA2451, a point in the circuit, traced hereinafter, for energizing the lower winding of the line switching relay R2530 and prepares, at RA2451 and RA2452, a circuit, traced hereinafter, for energizing the busy test relay R2460. At RA2454 and RA2455, the relay R2450 completes a circuit for energizing the two relays R2405 and R2435, this circuit extending from ground at RA2431 by way of C2481, RA2534, C2485, RA2455, RA2454, C2492, the test wiper 2554 and its associated twenty-fifth contact, C2494, RA2439, the lower winding of R2405 and the winding of R2435 to battery. When its lower winding is energized over the circuit just traced, the relay R2405 operates to complete, at RA2406, a holding circuit for itself, which holding circuit extends from ground at RA2431 by way of RA2406 and the upper winding of R2405 to battery. At RA2408, the relay R2405 prepares a circuit, traced hereinafter, for energizing the relay R2510. The relay R2435, upon operating, completes, at RA2438 and RA2439, a holding circuit for itself, which circuit may be traced as extending from ground at RA2431 by way of C2481, RA2534, C2485, RA2455, RA2454, RA2438, RA2439, the

lower winding of R2405 and the winding of R2435 to battery. Following the completion of this holding circuit, the relay R2435 opens, at RA2439 and its associated resting contact, a point in its operating circuit as traced above. At RA2436, the relay R2435 opens a point in the circuit, traced hereinafter, for energizing the lower winding of the busy test relay R2460. At RA2437, the relay R2435 prepares a point in an alternative circuit, traced hereinafter, for energizing the rotary switch operating magnet 2561.

At the end of the open circuit period of the first impulse, when the line relay R2420 is caused to reoperate, the operating magnet 2561 is deenergized and, in cooperation with its associated ratchet and pawl mechanism, steps the wipers of the rotary switch 2550 from their respective home positions to their respective first off-normal positions. Similarly, during each succeeding impulse of the first impulse series transmitted to the incoming connector switch of Figs. 24 and 25, the operating magnet 2561 of the switch 2550 is alternately energized and deenergized to drive the wipers 2551 to 2555, inclusive, over the contacts of their respective associated contact levels until, at the end of the first impulse series, the wipers are left standing in engagement with the contacts which correspond to the number of impulses in the series. During this series of impulses, the relay R2440, due to its slow-to-release characteristic, is held operated to maintain the relay R2450 energized.

In the illustrated arrangement of the incoming connector switch of Figs. 24 and 25, the lines terminating at the bank contacts of the rotary switch 2550 are divided into three groups. The first off-normal position of this rotary switch represents the preliminary or starting position for the selection of lines in the first line group, the lines of this group being terminated at the contact sets numbered from 2 to 8, inclusive. The ninth off-normal position of the switch represents the preliminary or starting position for the selection of lines in the second line group, the lines of this second group being terminated at the contact sets numbered from 10 to 19, inclusive. The twentieth off-normal position of the rotary switch is reserved as the preliminary or starting position for the selection of the lines of the third group, which lines are terminated at the contact sets numbered from 21 to 25, inclusive. Finally, the twenty-fifth set of contacts embodied in the rotary switch 2550 represents the home or normal position of the switch. With this arrangement, a first impulse series, comprising a single impulse, followed by a second series of from one to seven impulses, depending upon the line being called, must be transmitted to the incoming connector switch in order to select a subscriber's line in the first line group. If the desired line is in the second group of subscribers' lines, a first series of two to nine impulses, followed by a second series of from one to ten impulses must be transmitted to the incoming connector switch for the purpose of causing the wipers of the rotary switch 2550 to be operated into engagement with the contacts terminating the called line. In order to select a line in the third group of lines, a first series of ten impulses, followed by a second series of from one to five impulses, depending upon the line being called, are required to cause the desired line selection to be performed on the part of the incoming connector switch.

In the call under consideration, if the line 16 extending to the called substation T_9 is assumed to be the third line in the first group of lines, a first impulse series comprising a single impulse, followed by a second impulse series of three impulses, must be transmitted to the incoming connector switch of Figs. 24 and 25 in order to cause the wipers 2551 to 2555, inclusive, to be operated into engagement with the contacts terminating the conductors of the called line. At the conclusion of the first impulse series, therefore, the enumerated wipers are left standing in engagement with their respective associated first contacts. During the inter-digit pause between the first and second series of impulses transmitted to the incoming connector switch, the line relay R2420 is held operated for a sufficient time interval to permit the slow-acting relay R2440 to restore. Upon restoring, the relay R2440 opens, at RA2441, the holding circuit for R2450 and interrupts, at RA2442, a point in the previously traced alternative circuit for energizing the rotary switch operating magnet 2561. When the relay R2450 restores, it opens, at RA2451 and RA2452, a point in the circuit for energizing the busy test relay R2460 and prepares, at RA2451, the above-mentioned circuit for energizing the line switching relay R2530. At RA2454 and RA2455, the relay R2450 interrupts the previously traced holding circuit for the relay R2435, permitting the last-mentioned relay to restore. Following the restoration of R2435, the control apparatus embodied in the incoming connector switch of Figs. 24 and 25 is conditioned to respond to the second series of impulses transmitted thereto.

During the impulses of the second series, the line relay R2420 operates repeatedly to complete the previously traced operating circuit for the magnet 2561 so that the wipers of the rotary switch 2550 are moved over their respective associated contacts at the rate of one step for each impulse. Hence, at the conclusion of the second series of impulses, the wipers are left standing in engagement with the contacts terminating the conductors of the desired called line. The two relays R2440 and R2450 are caused to reoperate at the beginning of the first impulse of the second series and remain operated until shortly following the end of the impulse series.

Before describing the operation of the incoming connector switch to test the called line for the purpose of determining the idle or busy condition thereof, the mode of operation of this switch to select lines of the second and third line groups will briefly be considered. In this regard, it is pointed out above that, to select a line in the second group of lines, a first impulse series of two or more impulses must be transmitted to the switch so that, at the end of the series, the wipers 2551 to 2555, inclusive, occupy positions intermediate their first and tenth off-normal positions. With the wipers occupying one of these intermediate positions, a circuit is completed, during the interdigit pause between the first and second series of impulses transmitted to the switch and in response to the restoration of the relay R2450, for energizing the operating magnet 2561 by way of the circuit interrupting contacts associated with the armature 2562. Also, an alternative holding circuit is completed for maintaining the relay R2435 energized. This alternative holding circuit for R2435 may be traced as extending from ground as connected to the multiplied contacts numbered from 2 to 8, inclu-

sive, of the contact level associated with the test wiper 2554, by way of this wiper, C2492, RA2438, RA2439, the lower winding of R2405 and the lower winding of R2435 to battery. The circuit 5 for energizing the rotary switch operating magnet 2561 may be traced as extending by way of the grounded test wiper 2554, C2492, RA2454, RA2437, C2489, the armature 2562 and the winding of the magnet 2561 to battery. Due to the 10 circuit interrupting action of the armature 2562, the operating magnet 2561 operates, buzzer fashion, to drive the wipers of the rotary switch 2550 until they are moved to the preliminary or starting position for the selection of lines in the 15 second group, which position, in the arrangement illustrated, comprises the ninth off-normal position of the switch. When the test wiper 2554 is moved to this ninth off-normal position, it is disconnected from ground to interrupt the alternative operating circuit for the magnet 2561 and to open a point in the above-traced alternative holding circuit for the relay R2435. Thus, the 20 operation of the magnet 2561 is arrested and the relay R2435 is caused to restore. The manner 25 in which the wipers of the switch 2550 are operated from the ninth off-normal position to a position corresponding to a desired line in the 30 second group is exactly the same as set forth above with reference to the operation of the incoming connector switch to select the line 76 included in the first line group.

As indicated above, in the event the desired called line is included in the third group of lines terminating at the contact sets numbered from 35 21 to 24, inclusive, of the switch 2550, a first series of ten impulses is transmitted to the incoming connector switch so that the wipers of the rotary switch 2550 are operated to their respective tenth off-normal positions. It will be 40 observed that the tenth to nineteenth contacts of the level associated with the test wiper 2554 are also multiplied together and connected to ground so that the above-traced alternative holding circuit for R2435 and the alternative 45 operating circuit for the rotary switch operating magnet 2561 are completed during the interdigit pause between the first and second series of impulses and in response to the restoration of the relay R2450. Thus, the magnet 2561 is 50 caused to operate, buzzer fashion, to drive the wipers of the switch 2550 until they are positioned upon the contacts representing the preliminary or starting position for the selection of lines in the third group. More particularly, when 55 the wipers are operated to their respective twentieth off-normal positions, ground potential is removed from the test wiper 2554 to cause the deenergization and restoration of the relay R2435 and to arrest the operation of the rotary switch 60 operating magnet 2561. Following the operation of the wipers 2551 to 2555 to the preliminary or starting position for the selection of lines in the third line group, the incoming connector switch operates to select a desired line in this group in 65 the exact manner described above with reference to the selection of the called line 76 included in the first line group.

If the called line 76 is idle at the time it is selected by the incoming connector switch of 70 Figs. 24 and 25 in the manner explained above, negative battery potential is present upon the control conductor thereof. On the other hand, if the line is busy ground potential is present upon the control conductor of the line. Assuming the line to be idle, when the relay R2450 re-

stores shortly following the end of the second series of impulses transmitted to the incoming connector switch, the above-mentioned circuit is completed for energizing the lower winding of the switching relay R2530, this circuit extending from ground at RA2431 by way of RA2461, C2483, the lower winding of R2530, C2482, RA2451, RA2436, RA2407 and C2484 to battery as impressed upon the control wiper 2552 over the control conductor of the called line. When its lower winding is energized over this circuit, the slow-to-operate relay R2530 partially operates to complete, at the "X" contacts associated with RA2535, a circuit for energizing its upper winding, which circuit may be traced as extending from ground at RA2431 by way of C2481, RA2535 and the upper winding of R2530 to battery. When its upper winding is energized, the relay R2530 fully operates to complete, at RA2534, a path for impressing ground potential upon the control conductor of the selected called line, this path extending from ground at RA2431 by way of C2481, RA2434 and the test wiper 2552 to the control conductor of the called line. At RA2536, the relay R2530 opens a point in the previously traced circuit for energizing the rotary switch operating magnet 2561. At RA2538, the relay R2530 opens a point in the path, traced herein-after, for connecting the busy tone current source provided in the exchange E to the positive side of the loop circuit extending to the calling operator's position. At RA2532 and RA2537, the relay R2530 completes a circuit for projecting ringing current over the line to energize the signal device provided at the called substation. In the event the called line is of the duplex type, similar to that shown in Fig. 21, the path of the ringing current may be traced as extending from the ungrounded terminal of the ringing current source, not shown, by way of the exchange battery provided in the exchange E, the winding of the slow-acting ring cut-off relay R2540, RA2511, RA2521, RA2532, the wiper 2551, the negative side of the line extending to the called substation, and through the series connected condenser and ringer provided at the called substation to the grounded terminal of the ringing current source. On the other hand, if the called substation is of the single party type, such that the series connected ringer and condenser provided thereat are bridged between the line conductors of the called line, the return path of the ringing current may be traced as extending by way of the positive side of the called line, the wiper 2555, RA2537, RA2525, and RA2513 to the grounded terminal of the ringing current source. A portion of the ringing current is by-passed over the path including RA2531, the condenser 2558, C2479 and the loop circuit extending to the repeater 20 in the usual manner, so that a ring-back tone signal is transmitted to the calling operator to indicate that the ringing operation is being performed.

When the call is answered at the called substation T₂, a direct current bridge is connected between the line conductors of this line so that the ring cut-off relay R2540 is energized over the loop circuit just described. This relay now operates to complete, at RA2541, an obvious circuit for energizing the slave relay R2520, which latter relay, in turn, operates to complete, at the "X" contacts associated with RA2523, a holding circuit for itself. The holding circuit for the relay R2520 extends from ground at RA2431 by way of C2481, RA2523 and the winding of R2520 to battery. At RA2521, the relay R2520 opens a point in the

common portion of the above-described circuits for projecting ringing current over the called line and for transmitting ring-back tone current back over the loop circuit extending to the repeater 20. At RA2524, the relay R2520 opens a point in the circuit, traced hereinafter, for energizing the relay R2510. At RA2521 and RA2525 and their respective associated resting contacts, the relay R2520 opens two points in the circuit for energizing the ring cut-off relay R2540, whereby the last-mentioned relay is caused to restore, to open, at RA2541, the operating circuit for R2520. At RA2521 and RA2525 and their respective associated working contacts, the relay R2520 completes the desired talking connection between the calling operator's position and the called substation T₂. The completion of this talking circuit results in the energization of the battery reversing relay R2410 in series with the winding of the line balancing impedance element 2498. More particularly, this circuit may be traced as extending from ground at the upper terminal of the winding of R2410 by way of this winding, RA2474, C2495, RA2525, RA2537, the wiper 2555, the loop circuit extending to the called substation, the wiper 2551, RA2532, RA2521, C2479, RA2471 and the winding of the impedance element 2498 to battery. The current traversing this circuit serves to energize the transmitter provided at the called substation in the usual manner.

When energized over the circuit just traced, the relay R2410 operates to reverse, at its armatures RA2411 to RA2414, inclusive, battery potential back over the loop circuit extending to the repeater 20, thereby to reverse the direction of current flow through the left winding of the polarized relay R1640. The last-mentioned relay now operates to complete, at RA1642, an obvious circuit for energizing the battery reversing relay R1620. At RA1641, the relay R1640 completes an obvious circuit for energizing the relay R1645. The relay R1620, upon operating, moves its armatures RA1624 and RA1628 into engagement with their respective associated armatures RA1625 and RA1629, thereby to reverse battery back over the loop extending through the operated incoming connector switch of Figs. 12 and 13 to the trunk line terminating apparatus shown in the upper portion of Fig. 7. The resulting reversal of current flow through the upper winding of R790 causes this relay to operate and open the circuit for energizing the supervisory lamp associated with the link line utilized in completing the connection, all in the manner explained previously. At RA1627 and RA1627', the relay R1620, upon operating, completes obvious paths for short-circuiting the two windings of R1630, thereby to remove the impedance of these windings from the voice frequency current transmission circuit. At RA1622 and RC1623, the relay R1620, upon operating, disconnects the control conductor C1686 of the trunk line from the ground. At RA1621 and RA1622, the relay R1620 completes the previously mentioned path for impressing booster battery potential upon the control conductor C1686, this path extending from the negative terminal of the booster battery source 1687 by way of the resistor 1688, RA1651, RA1652, RA1621 and RA1622 to the control conductor C1686. The application of booster battery potential to this control conductor is without effect on the type of call here being considered. The relay R1645, upon operating, opens, at 75 RA1646 and its associated resting contact, a point

in the previously traced circuit for energizing the slow-to-release relay R1650 and completes, at RA1646 and its associated working contact, a holding circuit for itself, which holding circuit extends from ground at RA1651 by way of C1683, RA1646 and the winding of R1645 to battery. After a short time interval, the relay R1650 restores to open, at RA1651 and RA1652, a point in the above-traced path for impressing booster battery potential upon the control conductor C1686 and to complete, at RA1652 and RC1653, an alternative path extending from ground at RA1661 for maintaining ground potential upon the indicated control conductor. Following the restoration of the relay R1650, no further operation of the apparatus embodied in the operated switch train extended to the called substation T₉ occurs until the connection is released or until one of the called subscriber's attempts to resignal the operator in the exchange B.

If the called subscriber at the substation T₉ desires to recall the operator in the exchange B, he may do so by momentarily operating the hook switch provided at the called substation to open the loop circuit extending to the called substation and thus cause the deenergization of the battery reversing relay R2410. This relay, upon restoring, reverses battery back over the loop extending to the repeater 20, thereby to reverse the direction of current flow through the left winding of the relay R1640. The relay R1640 responds by restoring to open the operating circuit for the battery reversing relay R1620, which latter relay, in turn, restores, to reverse battery back over the loop extending to the trunk line terminating apparatus shown in the upper portion of Fig. 7. The relay R790 now restores to recomplete the circuit for energizing the supervisory lamp associated with the link line, such for example, as the line 552, utilized in completing the desired connection. Obviously, each time the loop circuit extending to the called substation is recompleted, following the momentary operation of the hook switch provided at the called substation to its normal position, the four relays R2410, R1640, R1620 and R790 are caused to reoperate, in the order named, whereby the above-mentioned supervisory lamp is deenergized. The intermittent illumination of this lamp serves to indicate to the operator that she is being recalled, whereupon she may reenter the connection and converse with the called subscriber to determine the service desired.

As explained previously, if the connection as routed to the incoming connector switch shown in Figs. 24 and 25 from the operator's position in the exchange B is to be extended to a subscriber's line of the multiplex type, a third series of impulses must be transmitted to the incoming connector switch in order to cause the station selecting apparatus associated with the called line to select the desired substation. For the purpose of conditioning the control apparatus embodied in the incoming connector switch to repeat the impulses of the third series to the line selecting apparatus associated with a line of the multiplex type, the relay R2510 is provided, which relay is arranged to be energized when the wipers of the rotary switch 2550 are operated into engagement with the contacts terminating a line of the multiplex type. More particularly, each of the contacts of the level associated with the wiper 2553 which corresponds to a line of the multiplex type is connected through a resistor to the exchange battery to provide a circuit for ener-

gizing the relay R2510. Thus, the twenty-second contact of the contact level associated with the wiper 2553 is connected through a resistor 2571 to the negative terminal of the exchange battery provided in the exchange E. Hence, when the wipers 2551 to 2555, inclusive, are operated into engagement with their respective associated twenty-second contacts in response to the dialing of two line selecting digits designating the line terminated at the twenty-second contact set of the rotary switch 2550, the above-mentioned circuit is completed for energizing the relay R2510, this circuit extending from ground at RA2408 by way of C2493, the winding of R2510, RA2524, the wiper 2553 and the resistor 2571 to battery. At the end of the second series of impulses transmitted to the incoming connector switch and when the relay R2450 restores in the manner explained above, the switching relay R2530 is caused to operate to perform the functions described previously. At RA2534, the relay R2530 completes the previously traced path for impressing ground potential upon the control conductor of the selected multiplex line. When energized over the circuit traced above, the relay R2510 operates to open, at RA2511, a point in the previously traced circuit for projecting ringing current over the selected called line and to prepare, at RA2512, a circuit, traced hereinafter, for energizing the relay R2500. At RA2513, the relay R2510 opens a point in the path for impressing ground potential upon the positive line conductor of the selected called line and completes the previously traced path for impressing negative battery potential upon the positive side of the selected called line. The last-mentioned path may be traced as extending from the negative terminal of the exchange battery provided in the exchange E by way of the resistor 2422', RA2423, C2491, RA2513, RA2525, RA2537, and the wiper 2555 to the positive line conductor of the selected line. When ground potential is impressed upon the control conductor of the selected line, the station selecting apparatus associated with the line is seized and conditioned to respond to negative battery impulses transmitted thereto over the positive side of the selected line.

During the impulses of the third impulse series transmitted to the incoming connector switch of Figs. 24 and 25, the line relay R2420 responds by opening and closing, at RA2423, a point in the above-traced path for impressing negative battery potential upon the positive side of the selected line. The station selecting apparatus responds to the pulses of negative battery potential transmitted thereto over this path by selecting the particular substation desired by the calling party. At the beginning of this third series of impulses, the two relays R2440 and R2450 are again caused to operate, in the manner explained previously. Upon operating, the relay R2450 completes a circuit for energizing the lower winding of the busy test relay R2460, this circuit extending from ground at RA2431 by way of C2481, RA2534, C2484, RA2407, RA2436, RA2451, RA2452 and the lower winding of R2460 to battery. When its lower winding is energized over this circuit, the relay R2460 operates to prepare, at RA2461, a holding circuit for itself, this holding circuit being completed shortly following the end of the third series of impulses transmitted to the incoming connector switch when the relay R2450 restores, and extending from ground at RA2431 by way of RA2461, RA2472, RC2453, RA2452 and the lower winding of R2460 to battery. At RA2464,

the relay R2460 prepares a point in the operating circuit for the relay R2500. When the relay R2450 restores at the end of the third series of impulses, it completes this operating circuit for the relay R2500, which circuit may be traced as extending from ground at RA2431 by way of C2481, RA2534, C2484, RA2407, RA2436, RA2451, C2482, RA2512, C2487, RA2464, C2486 and the winding of R2500 to battery. Upon operating, the relay R2500 completes, at RA2501, the previously traced circuit for projecting ringing current over the selected called line to energize the signal device provided at the called substation and for transmitting ring-back tone current back over the loop circuit extending to the repeater 20. Thus, the usual ring-back tone signal is transmitted to the calling telephone station. When the call is answered at the called substation, the substation selecting apparatus associated with the called line operates to impress ground potential upon the negative side of the selected called line, thereby to complete the previously traced circuit for energizing the ring cut-off relay R2540. Upon operating, the relay R2540 completes, at RA2541, the operating circuit for the relay R2520, which latter relay, in turn, operates to complete its holding circuit and to open, at RA2521, a point in the circuit by way of which ring-back tone current is transmitted to the repeater 20 and a point in the operating circuit for the relay R2540. At RA2521 and RA2525 and their respective associated working contacts, the relay R2520 completes the talking connection between the calling and called telephone stations and, in so doing, completes the previously traced circuit for energizing the battery reversing relay R2410 in series with the line balancing impedance element 2498. At RA2524, the relay R2520 opens a point in the above-traced operating circuit for the relay R2510, causing the last-mentioned relay to restore to open, at RA2512, the operating circuit for the relay R2500. Following the restoration of the three relays R2500, R2510 and R2540, no further relay operations occur in the incoming connector switch shown in Figs. 24 and 25 until the connection is cleared out at the called substation or until the connection is released at the operator's position in the exchange B.

As indicated previously, if a line selected by the incoming connector switch of Figs. 24 and 25 is busy at the time the wipers of the rotary switch 2550 are operated into engagement with the contacts terminating the conductors thereof, the control apparatus embodied in the incoming connector switch operates to return busy tone through the operated switch train to signal the calling operator in the exchange B. Thus, if the line 76 is busy at the time the call initiated at the operator's position is routed thereto, ground potential is present upon the control conductor thereof so that, when the wiper 2552 is moved into engagement with the contact terminating this control conductor, a circuit is completed for energizing the lower winding of the busy test relay R2460, this circuit extending by way of the grounded wiper 2552, C2484, RA2407, RA2436, RA2451, RA2452 and the lower winding of R2460 to battery. When energized over this circuit, the relay R2460 operates to prepare, at RA2461, a holding circuit for itself and to open, at RA2463, a point in the previously traced circuit for energizing the rotary switch operating magnet 2561. At RA2461 and its associated resting contact, the relay R2460 opens a point in the above-traced operating circuit for the line switching relay

R2530. At RA2464, the relay R2460 prepares the previously traced operating circuit for the relay R2500. At RA2465, the relay R2460 completes the above-mentioned path for effectively connecting the high potential terminal of the busy tone current source provided in the exchange E to the positive side of the loop circuit extending to the repeater 20. This path may be traced as extending by way of C2551, the condenser 2559, RA2538, C2497, RA2475, and RA2465 to the positive side of the talking circuit, and the completion thereof results in the transmission of the usual busy tone signal to the calling operator to indicate that the desired line is busy. Shortly following the operation of the relay R2460, the relay R2450 restores to complete the previously traced holding circuit for R2460.

When the operator in the exchange B receives the busy tone signal, she may either initiate the release of the partially established connection, in the manner explained hereinafter, or she may break in upon the previously established connection extending to the called substation T₉ and offer the call to the called subscriber. In order to break in upon the previously established connection extending to the called substation T₉, the operator in the exchange B momentarily operates the toll offering switch 753 to its off-normal position, thereby to impress ground potential upon the positive side of the loop circuit extending to the repeater 20. When ground potential is impressed upon the line conductor C1682, the series connected upper windings of the differentially wound relay R1630 and the line relay R1655 are short-circuited, while the respective lower windings of these two relays are held energized. The relay R1630 now operates to complete, at RA1631, an obvious path for impressing ground potential upon the trunk line conductor C2476 of the trunk line 31' and a path extending by way of the winding 1673, the left winding of the polarized relay R1640, the transformer winding 1674, RA1657 and RA1661 for impressing ground potential upon the other conductor C2477 of the trunk line 31'. When these two paths are completed, the respective lower windings of the two relays R2415 and R2420 embodied in the incoming connector switch of Figs. 24 and 25 are de-energized, causing the differentially wound relay R2415 to operate. Upon operating, the relay R2415 completes, at RA2416, a circuit for energizing the relay R2470, this circuit extending from ground at RA2431 by way of C2481, RA2534, C2485, RA2455, RC2456, RA2462, RA2416 and the winding of R2470 to battery. When energized over this circuit, the relay R2470 operates to complete, at the "X" contacts associated with RA2473, a path extending by way of RA2416 for short-circuiting the upper winding of R2460, thereby to render the relay R2460 slow to release. At RA2472, the relay R2470 opens the original holding circuit for R2460, as traced previously, and completes an alternative holding circuit therefor, this alternative circuit extending by way of the grounded wiper 2552, C2484, RA2472, RC2453, RA2452 and the lower winding of R2460 to battery. When the relay R2415 restores, in response to the release of the toll offering switch 753, it opens, at RA2416, a point in the above-traced path short-circuiting the upper winding of R2460, permitting this winding to be energized in series with the winding of R2470 over a circuit extending from ground at RA2431 by way of C2481, RA2534, C2485, RA2455, RC2456, RA2462, the upper winding of R2460, RA2473

and the winding of R2470 to battery. With the relay R2470 operated, the above-traced path by way of which busy tone current is projected over the established talking circuit to the calling operator's position is interrupted at RA2475. At its two armatures RA2471 and RA2474 and their respective associated working contacts, the relay R2470 completes the desired talking connection to the called line, whereupon the operator may offer the call to the called subscriber in the usual manner. It will be noted that the two condensers 2428 and 2429 are included in the talking circuit which is extended to the called line and, further, that talking battery is not impressed upon the loop circuit extending to the called substation through the windings of the battery reversing relay R2410 and the line balancing impedance element 2498. Thus, the completion of the bridging connection to the previously established talking circuit can in no way interfere with the release of the operated switch train by way of which the previously established talking circuit extends.

If the called subscriber accepts the toll call offered by the operator in the position B, the parties conversing over the previously established connection are instructed to hang up thereby to release the previously established connection and to free the called line 76. During the release of this previously established connection, ground potential is removed from the control conductor of the called line 76 and battery potential is substituted therefor. As a result, the lower winding of the busy test relay R2460 is deenergized. The busy test relay R2460 is now energized only by the current traversing its upper winding, which current is insufficient to maintain the relay operated, but retards the release thereof for a substantial time interval. At the end of this interval, the relay R2460 restores to open, at RA2462, the above-traced circuit for energizing its upper winding and the winding of R2470 in series, permitting the last-mentioned relay to restore. At RA2461 and its associated resting contact, the relay R2460 completes the previously traced circuit for energizing the lower winding of the line switching relay R2530. At RA2465, the relay R2460 interrupts the above-traced path for connecting the busy tone current source to the positive side of the talking circuit extending to the calling operator's position. When the relay R2470 restores, it reprepares, at RA2471 and RA2474, two points in the loop circuit to be extended to the called substation and opens, at RA2473, a point in its holding circuit as traced above. The relay R2530 operates, after an interval, to complete its holding circuit and to complete the above-traced circuit for projecting ringing current over the called line to energize the signal device at the called substation, all in the manner explained previously. When the call is answered at the called substation, the incoming connector switch of Figs. 24 and 25 operates to complete the desired talking circuit in the exact manner set forth above.

The release of an established connection extending to one of the lines terminating at the bank contacts of the incoming connector switch shown in Figs. 24 and 25 is entirely under the control of the operator in the exchange B. Thus, if the called subscriber is the first to hang up, the four relays R2410, R1640, R1620 and R190 are caused sequentially to restore, in the order named and in the manner explained previously, to cause the energization of the supervisory lamp

individual to the link line utilized in completing the connection between the calling and called substations. The continuous illumination of this lamp indicates to the operator that the connection routed by way of the link line is ready to be released. The manner in which the incoming connector switch shown in Figs. 12 and 13 is released when the operator in the exchange B clears out the connection is in all respects identical with the release of this switch as described in the preceding subsection. During the release of this switch, the loop circuit extending to the repeater 20 is interrupted, whereby the line relay R1655 is deenergized and restores. Upon restoring, this relay opens, at RA1657, a point in the loop circuit extending to the operated incoming connector switch of Figs. 24 and 25 and interrupts, at RA1656, the operating circuit for the hold relay R1660. The last-mentioned relay now restores to open, at RA1652, the circuit for energizing the right winding of the polarized relay R1640 in parallel with the winding of R1665. At RA1661, the relay opens the holding circuit for R1645, causing the last-mentioned relay to restore. When the relay R1665 restores, the line conductors of the trunk line 31' are disconnected from the line terminals of the repeating transformer 1670 and are connected to the line conductors of the link line extending to the line circuit 21. Following the restoration of R1665, the repeater 20 is completely released and is conditioned for further use. In this regard, it is pointed out that when the hold relay R1660 restores it opens, at RA1661, the path for impressing ground potential upon the control conductor C1683 and completes a path extending by way of the resistor 1663 for impressing negative battery potential upon the indicated control conductor, thereby to mark the repeater 20 as idle in the numerical switches having access thereto.

When the loop circuit extending to the incoming connector switch shown in Figs. 24 and 25 is interrupted, the line relay R2420 is deenergized and restores. Upon restoring, the relay R2420 opens, at RA2421, the operating circuit for the hold relay R2425, which latter relay restores, after an interval, to open, at RA2427, the operating circuit for R2430. When the relay R2430 falls back, it reprepares, at RA2432, the operating circuit for the relay R2400 and opens, at RA2431, a point in the common portion of the holding circuits for R2405, R2460, R2470, R2520 and R2530, causing any operated ones of these relays to restore. At RA2433, the relay R2430 completes a path for impressing ground potential upon the first, ninth and twentieth contacts of the contact level associated with the test wiper 2554, this path extending from ground at RA2421 by way of RA2433 and C2490 to each of the three enumerated contacts. At this time, ground potential is present upon all of the contacts of the level associated with the test wiper 2554 with the exception of the twenty-fifth contact, which latter contact represents the home position of the switch. Hence, when the relay R2430 restores, it completes, at RA2434', an alternative circuit for energizing the relay R2435, this circuit extending by way of the grounded test wiper 2554, C2492, RA2454, RA2434', and the winding of R2435 to battery. When energized over this circuit, the relay R2435 operates to complete, at RA2437, an alternative circuit for energizing the rotary switch operating magnet 2561, this circuit extending by way of the ground-

ed test wiper 2554, C2482, RA2454, RA2437, C2489, the armature 2462 and the winding of the magnet 2561 to battery. Due to the circuit interrupting action of the contacts associated with the armature 2562, the magnet 2561 operates, buzzer fashion, to drive the wipers of the rotary switch 2550 until they are moved into engagement with their respective twenty-fifth contacts representing the home position of the switch. When the test wiper 2554 is moved out of engagement with its associated twenty-fourth contact, ground potential is removed therefrom so that no further circuit is available for energizing the operating magnet 2561 and the operation of the rotary switch 2550 is arrested. When ground potential is removed from the wiper 2554, the relay R2435 is deenergized and restores. Thus, the control apparatus embodied in the incoming connector switch of Figs. 24 and 25 is returned to normal and this switch is conditioned for further use.

SUBSECTION J.—Trunk call routed from exchange B directly to exchange E

As pointed out in Section 1 of the specification, a call originating at a substation associated with a line terminating at the exchange B may be routed directly to a substation line terminating at the exchange E without the intervention of the operator located in the exchange B or the intervention of the operator located in the exchange A. Thus, the connector portion of the finder-connector link shown in Figs. 19 and 20 has direct access to one or more repeaters associated with trunk lines extending to the exchange E. With this arrangement, if a calling subscriber at a substation associated with a line terminating at the exchange B dials the appropriate line selecting digits, the connection is forwarded over one of the last-mentioned group of trunk lines to an incoming connector switch located in the exchange E. For example, if the above-described call originating at the substation T₁ is to be routed to a substation line terminating at the exchange E and the local finder-connector link shown in Figs. 19 and 20 is assigned to the use of the call, the calling subscriber, upon dialing the line selecting digits designating the group of trunk lines extending to the exchange E may initiate the operation of the connector portion of this link to seize an idle one of the group of repeaters individually associated with the trunk lines extending to the exchange E. Thus, if the repeater 20 associated with the trunk line 31' is the first available idle trunk line of the indicated group, the connector portion of the local finder-connector link shown in Figs. 19 and 20 operates in the manner explained previously to seize the trunk line 38 extending to this repeater. When the trunk line 38 is seized, the calling loop circuit is switched through to the repeater 20 and the line relay R1655 is energized thereover. From this point on, the manner in which the connection is routed to the desired line terminating at the exchange E is exactly the same as explained in the preceding subsection. When the call is answered at the called substation to cause the sequential operation of the relays R1640 and R1620 in the manner previously explained, the resulting reversal of battery over the line conductors C1681 and C1682 of the trunk line 31' is without effect. On the other hand, the momentary application of booster battery potential to the control con-

ductor C1686 caused by the operation of the relay R1620 and the subsequent restoration of the relay R1650, in the manner explained above, is effective to energize the operating magnet of the call metering device associated with the calling substation. Thus, in the case here being considered, wherein the call originates at the substation T₁, the operating magnet 2176 of the metering device associated with this substation is energized in response to the operation of the relay R1620 over a circuit which may be traced as extending from the negative terminal of the booster battery source 1687 by way of the resistor 1688, RA1651, RA1652, RA1621, RA1622, the control conductor C1686, the wiper 1902, C1987, C2042, the springs 2059, RA2023, RA2052, RA2053, the wiper 2072, C2178, RA2123, RA2151 and the winding of the magnet 2176 to ground. The resulting momentary operation of the operating magnet 2176 causes the metering device associated with the calling substation T₁ to register the call. Aside from this difference pertaining to the feature of utilizing reverse battery for supervisory purposes when the call originates at the operator's position in the exchange B and the use of booster battery control of the call registering device associated with the calling substation when the call originates at a local substation, the mode of completing the connection directly to the desired substation line terminating at the exchange E and of releasing the connection following its completion is substantially the same as described in the preceding subsection.

SUBSECTION K.—Trunk call routed from the exchange B directly to the exchange F

The arrangement of the system is such that, when the operator in the exchange B is not on duty, calls originating at substations associated with lines terminating at this exchange and intended for substations connected to lines extending to the exchange F may be routed to the desired substation without the intervention of an operator. Thus, when the operator in the exchange B is not on duty, the contact springs of the transfer switch 600 occupy the positions illustrated in the drawings so that the conductors of the trunk line 41 are connected by way of the contact springs 824, 826, 827 and 829 to the conductors of the trunk line 42 extending to the automatic switching equipment provided in the exchange F. With this arrangement, if a calling subscriber at a substation associated with a line terminating at the exchange B initiates a call and dials the appropriate line selecting digits, the connection may be forwarded by way of the repeater illustrated in Fig. 14, the trunk lines 41 and 42 and the automatic switching equipment provided in the exchange F to the desired called substation. For example, if the above-described call originating at the substation T₁ is to be routed to a substation line terminating at the exchange F and the local finder-connector link shown in Figs. 19 and 20 is assigned to the use of the call, the calling subscriber, upon dialing the line selecting digits designating the trunk line 37' may initiate the operation of the connector portion of this link to seize the trunk line 37' extending to the repeater shown in Fig. 14. When this trunk line is seized, the calling loop circuit is switched through to the indicated repeater and the line relay R1430 is energized thereover. Upon operating, the relay R1430 com-

plete, at RA1432, an obvious circuit for energizing the slow-acting hold relay R1405, which latter relay, upon operating, completes, at RA1406, an obvious circuit for energizing the slow-to-release relay R1400 in parallel with the lower winding of the relay R1420. At RA1431, the line relay R1430 prepares a loop circuit to the automatic switching equipment provided in the exchange F. At RA1407, the hold relay R1405, upon operating, completes an obvious path for impressing ground potential upon the control conductors C1376 and C1461, thereby to mark the repeater of Fig. 14 as busy and to maintain the local finder-connector link of Figs. 19 and 20 operated. At RA1407, a circuit is also completed for energizing the slow-to-release relay R1415, this circuit extending from ground by way of RA1407, RA1411 and the winding of R1415 to battery. When the relay R1400 operates, it completes, at RA1401 and RA1402 and their respective associated working contacts, the above-mentioned loop circuit to the exchange F, thereby to cause the seizure of the incoming connector switch terminating the distant end of the trunk line 42. When this loop circuit is completed, the upper winding of the relay R1420 is energized thereover but at this time the direction of current flow over the loop and through the upper winding of R1420 is such that the relay does not operate. When the relay R1415 operates, it prepares, at RA1416 and RA1417 a path, traced hereinafter, for impressing booster battery potential upon the control conductor C1461 of the trunk line 31. Following the completion of the loop circuit in the manner explained above, the repeater shown in Fig. 14 is conditioned to repeat the impulses of additional digits dialed at the calling substation to the operated incoming connector switch terminating the trunk line 42 and located in the exchange F. During the dialing operation, the line relay R1430 follows the impulses and, by interrupting, at RA1431, the loop circuit extending to the exchange F, functions to repeat the impulses to the incoming connector switch terminating the distant end of the trunk line 42. Thus, the connection may be routed to the desired called line in the exact manner explained above with reference to the incoming connector switch shown in Figs. 24 and 25 and located in the exchange E. Assuming that the called line is idle, and, further, that the call is answered at the called substation, the battery reversing relay provided in the operated incoming connector switch operates to reverse the direction of current flow over the loop circuit extending back to the repeater shown in Fig. 14. The relay R1420 responds to this battery reversal by operating to complete, at RA1422, an obvious circuit for energizing the relay R1410 and to complete, at RA1421, an obvious circuit for energizing the battery reversing relay R1440. When the last-mentioned relay operates, it short-circuits, at its two armatures RA1441 and RA1447, the respective windings of the differentially wound relay R1430 and actuates its armatures RA1442, RA1443, RA1445 and RA1446 to reverse the battery connections to the line conductors C1375 and C1377 of the trunk line 35. This last-mentioned operation on the part of the relay R1440 is without effect on the type of call here being considered. At RA1449 and RC1449', the relay R1440 disconnects the control conductor C1461 from ground and, at RA1448 and RA1449, it completes the above-mentioned path

for impressing booster battery potential upon the indicated control conductor. This path may be traced as extending from the negative terminal of the booster battery source, not shown, by way of the resistor 1456, RA1416, RA1417, RA1448 and RA1449 to the control conductor C1461, and the completion thereof results in the energization of the call registering device associated with the calling substation in the manner explained previously. The relay R1410, upon operating, completes, at RA1411, a holding circuit for itself, which holding circuit extends from ground at RA1407, by way of RA1411 and the winding of R1410 to battery. At RA1411 and its associated resting contact, the relay R1410 opens a point in the above-traced operating circuit for the slow-to-release relay R1415. The last-mentioned relay restores, after an interval, to open, at RA1416 and RA1417, a point in the above-traced path for impressing booster battery potential upon the control conductor C1461. At RA1417 and RC1418, the relay R1415, upon restoring, completes an alternative path for grounding the indicated control conductor, this alternative path extending from ground at RA1407 by way of RC1418, RA1417, RA1448 and RA1449 to the control conductor C1461. The release of the connection as established by way of the repeater shown in Fig. 14 and the trunk lines 41 and 42 to a substation associated with a line terminating at the exchange F is under the control of the calling subscriber. More particularly, when the call is cleared out at the calling substation, the loop circuit extending through to the repeater of Fig. 14 is interrupted to cause the deenergization and restoration of the line relay R1430. This relay, upon restoring, opens, at RA1431, the loop circuit extending to the operated incoming connector switch in the exchange F and interrupts, at RA1432, the above-described operating circuit for the hold relay R1405. When the loop circuit extending to the operated incoming connector switch located in the exchange F is interrupted, the release of this switch is initiated in the manner explained previously with reference to the incoming connector switch shown in Figs. 24 and 25. When the hold relay R1405 restores, it opens, at RA1406, the above-described circuit for energizing the relay R1400 in parallel with the lower winding of R1420, causing both of these relays to restore. At RA1407 and its associated working contact, the relay R1405 opens the above-traced holding circuit for the relay R1410 and interrupts the path for maintaining ground potential upon the control conductors C1376 and C1461. At RA1407 and its associated resting contact, the relay R1405 completes a path extending by way of the resistor 1455 for impressing negative battery potential upon each of the two enumerated control conductors, thereby to mark the repeater shown in Fig. 14 as idle. When the relay R1420 restores, it opens, at RA1421, the operating circuit for the battery reversing relay R1440, causing the last-mentioned relay to restore. Thus, the repeater shown in Fig. 14 is entirely released and is conditioned for further use. The release of the local finder-connector link illustrated in Figs. 19 and 20 is initiated when ground potential is removed from the control conductor C1461 of the trunk line 31', the manner in which the release of this link is effected being exactly as set forth previously in this section—Subsection C.

SECTION 8

SUBSECTION A.—Local connection completed between two substations associated with lines terminating at the exchange C

Referring now more particularly to the operation of the apparatus illustrated in Figs. 28, 29, 30, 33 and 34 to set up a connection between two substation lines terminating at the exchange C and considering, by way of example, a call initiated at the substation T₄ and intended for the subscriber at the substation T₅, the operation of the apparatus is initiated when the calling subscriber at the substation T₄ removes his receiver from its hook. The usual direct current path bridging the line conductors C2875 and C2877 of the calling line 59 is completed when the receiver at the substation T₄ is removed from its supporting hook or cradle. The line circuit 55 responds to the completion of this path by operating to impress battery potential upon the control conductor C2876 of the line 59, thereby to mark the calling line 59 in the bank contacts of the finder switch 2800. The line circuit 55 also operates to impress ground upon the distributor start conductor C3433, thereby to initiate the operation of the distributor illustrated in Fig. 30. More particularly, when ground potential is applied to C3433, the start relay R3050 is energized and operates to prepare, at RA3053, a circuit, traced hereinafter, for energizing the lower winding of the relay R3040. At RA3052, the relay R3050 completes a circuit for energizing the relay R3000, which circuit may be traced as extending by way of the grounded conductor C3433, RA3052, the resistor 3054, RA3022, RA3012 and the winding of R3000 to battery. At RA3051, the relay R3050 prepares a circuit, traced hereinafter, for energizing the operating magnet of the finder switch embodied in the switching selector repeater assigned to the use of the calling line. The relay R3000, upon operating, completes, at its armatures RA3001, RA3002, etc., circuits for energizing the respective slow-to-operate link selecting relays which individually correspond to idle ones of the switching selector repeater links located in the exchange C. Thus, the relay R3020 individually corresponding to the link shown in Figs. 28 and 29 is energized over a circuit which may be traced as extending from ground, at RA2914, by way of C2871, R2815, the guard conductor C3055, RA3002 and the winding of R3020 to battery. In a similar manner, the relay R3010 is energized over a circuit including the guard conductor extending to the second link. Each of these two relays and the other similar relays embodied in the distributor, upon operating, completes a holding circuit for itself, the holding circuit for the relay R3020 extending by way of the grounded guard conductor C3055, RA3024 and the winding of R3020 to battery, and the holding circuit for the relay R3010 extending by way of the grounded guard conductor of the second link, RA3014, and the winding of R3010 to battery. The relay R3020, upon operating, actuates its armatures RA3021, RA3022 and RA3023 into engagement with their respective associated working contacts, thereby to connect these armatures to the magnet, hold and test conductors C3058, C3057 and C3056, respectively, which extend to the link illustrated in Figs. 28 and 29. At RA3022 and its respective associated resting contact, the relay R3020 interrupts the above-traced operating circuit for R3000, causing the 75

last-mentioned relay to restore to open points in the respective operating circuits for the link select relays R3010, R3020, etc.

At RA3022 and its associated working contact, the relay R3020, upon operating, completes a circuit for energizing the line relay R2820, this circuit extending by way of the grounded start conductor C3433, RA3052, the resistor 3054, RA3022, C3051 and the upper winding of R2820 to battery. The relay R2820, upon operating, completes, at RA2822, an obvious circuit for energizing the slow-acting hold relay R2825. At RA2821, the relay R2820 bridges the series connected upper winding of R2830 and the winding of the impedance element 2835 between the trunk line conductors C2865 and C2874. The hold relay R2825, upon operating, opens, at RA2829, a point in the circuit, traced hereinafter for energizing the release magnet 2904 of the minor switch 2900, and prepares, at RA2828, a circuit for energizing the minor switch operating magnet 2903. At RA2826, the relay R2825 prepares a holding circuit, traced hereinafter, for the relay R2810 and also a path for impressing ground potential upon the control conductor C2876 of the calling line 59. At RA2827, the relay R2825 completes a circuit for energizing the slow-to-operate relay R2940, this circuit extending from ground by way of RA2827, C2867, RA2951, RA2931, the winding of R2940 and the resistor 2946 to battery. The relay R2940 operates after an interval to complete, at RA2944, a holding circuit for itself, which holding circuit extends from ground at RA2821 by way of C2867, RA2951, RA2944, the winding of R2940 and the resistor 2946 to battery. At RA2941, the relay R2940 completes a circuit for energizing the heating coil 2858 of the thermal relay 2857, this circuit extending from ground by way of RA2941, RA2911, C2866, the heating coil 2858 and the resistor 2859 to battery. At RA2942, the relay R2940 opens a point in the circuit, traced hereinafter, for energizing the relay R2970. At RA2943, the relay R2940 completes a circuit for energizing the two windings of R2960 in series, which circuit may be traced as extending from ground by way of RA2827, C2867, RA2951, RA2943 and the two windings of R2960 to battery. At RA2945, the relay R2940 completes a circuit for energizing the winding of R2920 in series with the winding of the relay R2930, this circuit extending from ground at RA2827 by way of C2867, RA2945, the winding of R2930 and the winding of the relay R2920 to battery.

When energized over the above-traced circuit, the relay R2960 partially operates to close the "X" contacts associated with RA2963 and RA2964. If, at the time this partial operation of R2960 occurs, the wipers of the switch 2980 are standing in engagement with the contacts corresponding to a local connector switch in the exchange C or to a busy outgoing repeater, ground potential is present upon the wiper 2982 so that a path is completed for short-circuiting the upper winding of R2960 before this relay completes its operation. The short-circuiting path may be traced as extending by way of the grounded wiper 2982, RA2962, RA2964, the upper winding of R2960, RA2943, RA2951, and C2867 back to ground at RA2827. The completion of this path serves to prevent the relay R2960 from fully operating. The presence of ground potential upon the wiper 2982 also results in the energization of the operating magnet 2985 over a circuit extending by way of RA2962, RA2963, RA2973, the armature 2986 and the winding of

the magnet 2985 to battery. Due to the circuit interrupting action of the springs associated with the armature 2986, the magnet 2985 operates to open its own operating circuit and to condition the associated ratchet and pawl mechanism to step the wipers of the switch 2980 one step. When the magnet 2985 is deenergized, the associated ratchet and pawl mechanism operates to step the wipers 2981 to 2984, inclusive, one step or into engagement with the next succeeding set of contacts. If this next set of contacts corresponds to a second busy repeater or to a local connector switch, the magnet 2985 is again energized over the above-traced circuit including the grounded wiper 2982 and operates to cause the enumerated wipers to be stepped a second step. The stepping operation of the switch wipers 2981 to 2984, inclusive, continues until such time as the wiper 2982 is moved into engagement with a contact terminating the control conductor of a trunk extending to an idle repeater, the idle condition of the repeater being indicated by the absence of ground potential upon the control conductor of the trunk line extending thereto. For example, if the repeater illustrated in Figs. 26 and 27 is idle, the wipers of the switch 2980 are stepped three steps from the position illustrated in the drawing, at which time the wiper 2982 is moved into engagement with the contact terminating the control conductor C2895. Since the wiper 2982 is now disconnected from ground, no further circuit is available for energizing the magnet 2985 and the stepping operation of the switch 2980 is arrested. Also, when ground is removed from the wiper 2982, the above-traced path short-circuiting the upper winding of R2960 is opened, permitting the two windings of this relay to be energized in series. The relay R2960 now completes its operation to open, at RA2962 and its associated resting contact, a further point in the operating circuit for the magnet 2985 and a further point in the path for short-circuiting its own upper winding. At RA2962 and its associated working contact, the relay R2960 completes an obvious path for impressing ground potential upon the control conductor of the trunk line 63 extending to the selected repeater. At RA2961 and RA2965, the relay R2960 completes a loop circuit, traced hereinafter, and extending to the selected repeater, thereby to cause the seizure of this repeater.

The two relays R2920 and R2930 operate when energized in series over the circuit traced previously. The relay R2920, upon operating, completes, at RA2922, an obvious holding circuit for maintaining the respective windings of R2930 and R2920 energized. At RA2923, the relay R2920 prepares a path, traced hereinafter, for short-circuiting the winding of R2930. At RA2924, the relay R2920 prepares a circuit for energizing the release magnet 2904 embodied in the minor switch 2900. The relay R2930, upon operating, opens, at RA2932, a point in the path for short-circuiting its own winding. At RA2933, the relay R2930 prepares a path, traced hereinafter, for short-circuiting the winding of R2940. At RA2934, the relay R2930 opens a point in the circuit, traced hereinafter, for energizing the release magnet 2904. Following the selection of an idle repeater and the operation of the two relays R2920 and R2930 in the manner just explained, the switching selector repeater illustrated in Figs. 28 and 29 is conditioned to respond to

the first series of impulses dialed at the calling substation.

As indicated above, when the relay R3020 operates, a circuit is completed for energizing the operating magnet 2804 of the finder switch 2800, this circuit extending from ground at RA3031 by way of RA3051, RA3041, RA3021, C3058 and the winding of the magnet 2804 to battery. When energized over this circuit, the magnet 2804 attracts its associated armature 2805 to complete a circuit for energizing the upper winding of the interrupter relay R3040, this circuit extending from ground by way of the armature 2805, the interrupter conductor C3059 and the upper winding of R3040 to battery. Upon operating, the relay R3040 opens, at RA3041, a point in the circuit, traced above, for energizing the operating magnet 2804. When this magnet is deenergized, its armature 2805 is restored to open the operating circuit for R3040, causing this relay to restore to recomplete the circuit for energizing the magnet 2804. The interrelated operation of the interrupter relay R3040 and the operating magnet 2804 continues until the wipers of the finder switch 2800 are driven into engagement with the contacts terminating the calling line 59, it being pointed out that, during each cycle of operation of the relay R3040 and the magnet 2804, the wipers 2801, 2802, 2803 and 2803' are operated one step. When the enumerated wipers are moved into engagement with the contacts terminating the conductors C2875, C2876, C2877 and C2878 of the calling line 59, a circuit is completed for energizing the upper winding of the switching relay R2810 in series with the respective lower windings of R3030 and R3040. This circuit may be traced as extending from ground at RA3053 by way of the lower winding of R3040, the lower winding of R3030, RA3023, C3056, the upper winding of R2810, the wiper 2802, the control conductor C2876 and the winding of the cut-off relay embodied in the line circuit 55 to battery. The relay R3030 operates immediately this test circuit is completed, and completes, at RA3032, an obvious holding circuit for the relay R3050. At RA3031 and its associated resting contact, the relay R3030 opens a point in the above-traced circuit for energizing the operating magnet 2804. At this same armature and its associated working contact, the relay R3030 completes a holding circuit for itself, which holding circuit extends from ground at RA3031 by way of the upper winding of R3030, RA3021, C3058 and the winding of the magnet 2804 to battery. Due to the relatively high resistance of the upper winding of the relay R3030, the magnet 2804 is insufficiently energized to operate when this holding circuit is completed. The energization of the lower winding of R3040 over the above-traced circuit serves to maintain this relay operated independently of the energized or deenergized condition of its upper winding, thereby further to insure the discontinuance of the operation of the finder switch 2800. When the circuit traced above and extending through the winding of the cut-off relay embodied in the line circuit 55 is completed, this cut-off relay operates in the usual manner to disconnect the distributor start conductor C3433 from ground and to disconnect the windings of the line relay embodied in the line circuit 55 from the line conductors C2875 and C2877.

The switching relay R2810 operates to close the "X" contacts associated with RA2812 when its upper winding is energized over the above-

traced test circuit. At these contacts a circuit is completed for energizing the lower winding of R2810, this circuit extending from ground by way of the thermostatic element 2861, the contacts 2864, RA2828, RA2812 and the lower winding of R2810 to battery. The relay R2810 now fully operates to complete, at RA2813, a path for applying ground potential to the control conductor C2816 of the calling line 59, which path may be traced as extending from ground by way of the thermal element 2861, the contacts 2864, RA2828, RA2812, RA2813 and the wiper 2802 to the control conductor C2816. At its two armatures RA2811 and RA2816, the relay R2810 upon fully operating extends the calling loop circuit to the line terminals of the line relay R2820, thereby to hold this relay energized after the distributor is released and the operating circuit for this line relay is interrupted. The application of ground potential to the control conductor C2816 serves to maintain the line 59 marked as busy until the connection is released. At RA2815, the relay R2810 opens a point in the previously traced path by way of which ground potential is impressed upon the guard conductor C3055. When ground potential is removed from the guard conductor C3055 the relay R3020 is deenergized and restores, after an interval, to open, at RA3021, the holding circuit for the relay R3030. The last-mentioned relay, upon restoring, opens, at RA3032, the holding circuit for the start relay R3050. When the start relay R3050 restores, the distributor illustrated in Fig. 30 is conditioned to respond to the initiation of a second call by assigning the next available idle switching selector repeater link to the line upon which the next call originates.

If, with the link illustrated in Figs. 28 and 29 busy and the second link corresponding to the relay R3010 idle, a second call is initiated on one of the lines extending to the exchange C, the distributor shown in Fig. 30 operates to assign the second link to the calling line upon which the second call originates. More particularly, when the second call is initiated, the line circuit associated with the calling line operates to impress ground potential upon the distributor start conductor C3433 thereby to energize the start relay R3050. Since the second link is idle the relay R3010, corresponding thereto, is operated and, hence, the operation of the start relay R3050 results in the application of ground potential to the hold conductor extending to the second link, and in the completion of a circuit extending by way of RA3051, RA3041, RA3021 and RA3011 for energizing the operating magnet of the finder switch embodied in the second link. Thus, the operation of the finder switch in the second link is initiated, the operating magnet of this switch interacting with the interrupter relay R3030 in the manner just described so that the wipers of the finder switch embodied in the second link are driven to a position corresponding to the second calling line. When this second calling line is found, the test relay R3030 operates to arrest the stepping operation of the finder switch embodied in the second link, and the switching relay embodied in the second link operates to open the holding circuit for the relay R3010. Upon restoring, the relay R3010 transfers the control circuits to the guard, test, hold and magnet conductors extending to the next available idle link. Thus, the links corresponding to the relays R3010, R3020, etc., are successively assigned to successive calling lines until

the last available idle link becomes busy. When all of the available links have been successively assigned for use and a call is thereafter initiated, the resulting operation of the start relay R3050 causes the operating circuit for the relay R3000 to be completed in the manner explained above. The relay R3000, upon operating, again completes the respective operating circuits for the link select relays which correspond to idle ones of the links. Thus, if the relay R3000 is caused to reoperate at a time when the link corresponding to the relay R3010 is idle and the link illustrated in Figs. 28 and 29 corresponding to R3020 is busy, the relay R3010 is caused to reoperate to prepare the start circuits extending to the associated link, whereas the relay R3020 remains in its restored position. In a similar manner, the other link select relays corresponding to idle links are caused to reoperate in response to the operation of R3000 while the link select relays corresponding to busy links remain in their respective restored position. In this regard, it is pointed out here that each time a link, as, for example, the link shown in Figs. 28 and 29, becomes idle following its use, ground potential is impressed upon the guard conductor extending thereto to prepare the operating circuit for the associated link select relay. If a call is initiated at a time when all of the links are busy, the control circuits which are controlled by the respective link select relays, the relay R3000 and the start relay R3050 are switched through to an all-links-busy meter, not shown, in the usual manner. Although not illustrated, provisions may also be made for returning busy tone to a calling subscriber who initiates a call at a time when all of the links provided in the exchange C are busy.

After the wipers of the switch 2980 are driven into engagement with the contacts terminating the trunk line 63 and when the switching relay R2980 operates, all in the manner explained above, the line relay R2775 embodied in the repeater illustrated in Figs. 26 and 27 is energized over a loop circuit which may be traced as extending from ground at the upper terminal of the lower winding of R2775 by way of this winding, C2894, the wiper 2984, RA2965, RA2952, C2874, the winding of R2835, the upper winding of R2830, RA2821, C2865, RA2961, the wiper 2981, C2896, and the upper winding of R2775 to battery. Since the direction of current flow over this loop circuit is such that the two windings of R2830 are differentially energized, the relay R2830 does not operate at this time. The relay R2775, on the other hand, operates to complete, at RA2776 an obvious circuit for energizing the slow-acting hold relay R2780. This hold relay, upon operating, completes, at RA2781, an obvious path for impressing ground potential upon the control conductor C2895 and completes, at RA2782, a circuit for energizing the slow-acting relay R2670. The last-mentioned circuit extends from ground at RA2782 by way of RA2736, C2682, RA2657 and the winding of R2670 to battery. Upon operating, the relay R2670 completes, at RA2672 and RA2673, the respective operating circuits for the relays R2630 and R2645. The relay R2630, upon operating, connects, at RA2631 and RA2633, the conductors of the trunk line 31 to opposite terminals of the alternating current source provided in the exchange C, and completes, at RA2632, the above-mentioned operating circuit for the relay R2660. The relay R2645, upon operating, disconnects at RA2646

and RA2647, the line conductors of the trunk line 31 from the line terminals of the repeating transformer windings 2616 and 2617. The relay R2660, upon operating, completes, at RA2662, an obvious operating circuit for the relay R2655 and completes, at RA2665, a circuit extending by way of C2693 and RA2783 for energizing the relay R2730. The relay R2730, upon operating, completes, at RA2738, a holding circuit for itself, this holding circuit extending from ground at RA2717 by way of RA2738', the winding of R2730 and the resistor 2731' to battery. At RA2731 and RA2739, the relay R2730 extends the loop circuit to the line terminals of the repeating transformer 2615. At RA2736, the relay R2730 opens a joint in the above-traced operating circuit for the relay R2670, this circuit further being interrupted at RA2657 in response to the operation of the relay R2655. The relay R2670, upon restoring, opens points in the respective operating circuits for the relays R2630, R2645 and R2660. Thus, the five relays R2630, R2645, R2655, R2660 and R2670 are caused to restore. When the relay R2630 restores, it disconnects the line conductors of the trunk line 31 from the source of alternating current provided in the exchange C, thereby to terminate the seizing pulse of alternating current transmitted by way of this line to the repeater illustrated in Figs. 17 and 18. Also, when the two relays R2630 and R2645 restore, the line conductors of the trunk line 31 are again connected to the line terminals of the repeating transformer windings 2616 and 2617. Following the restoration of the five relays enumerated above, the repeater illustrated in Figs. 26 and 27 is conditioned to respond to the impulses transmitted thereto by way of the switching selector repeater illustrated in Figs. 28 and 29. The repeater located in the exchange B and associated with the trunk line 31 responds to the seizing pulse of alternating current transmitted thereto in the manner just explained by routing the connection to a local finder-connector link provided in the exchange. More particularly, when alternating current is projected over the conductors of the trunk line 31, the alternating current relay R1815 operates to open, at RA1816, the junction point between the transformer winding 1874 and the condenser 1876 and to complete, at RA1817, a circuit for energizing the upper winding of R1750. The last-mentioned circuit extends from ground at RA1817 by way of C1790, RA1737', RA1756 and the upper winding of R1750 to battery. When its upper winding is energized over this circuit, the relay R1750 partially operates to complete, at the "X" contacts associated with RA1754, a path for short-circuiting its lower winding, which path may be traced as extending from ground by way of RA1754, RC1748, RA1747, the lower winding of R1750, RA1756, RA1737' and C1790 back to ground at RA1811. When the seizing pulse of alternating current projected over the trunk line 31 is terminated, the relay R1815 restores to open, at RA1817, a point in the short-circuiting path just traced. The two windings of R1750 are now energized in series over a circuit which may be traced as extending from ground at RA1754 by way of RC1748, RA1747 and the two windings of R1750 to battery. The relay R1750 now fully operates to complete, at RA1752, a path extending by way of RA1701 for applying ground potential to the control conductor C1379 of the trunk line 32, thereby to guard the repeater shown in Figs. 17 and 18 against seizure by one of the numerical

switches provided in the exchange B. At RA1753, the relay R1750 completes an obvious path for applying ground potential to the fifth contact of the inner row of contacts embodied in the bank contact field of the minor switch 1770. At RA1753, the relay R1750 also prepares operating circuits for the two relays R1712 and R1720. At RA1756, the relay R1750 prepares a circuit for energizing the lower winding of the relay R1870 in parallel with the winding of the slow-acting relay R1760. At RA1758, the relay R1750 completes a circuit for energizing the slow-to-release relay R1865, this circuit extending from ground by way of RA1758, C1794, RA1871, RA1851, and the winding of R1865 to battery. The last-mentioned relay, upon operating, prepares, at RA1866, a circuit for energizing the relay R1850 and prepares, at RA1867, a locking circuit for itself. At RA1751, RA1755 and RA1759, the relay R1750 completes a loop circuit extending by way of the link line 45 to the line circuit illustrated in Fig. 23. At RA1751, the relay R1750 completes a circuit for energizing the upper winding of R1765 in parallel with the lower winding of R1830, one branch of this circuit extending from ground at RA1757 through the upper winding of R1765 to battery, and the other branch extending from ground at RA1751 by way of C1792, RA1854 and the lower winding of R1830 to battery. The relay R1765 does not operate at this time, since its two windings are differentially energized. The relay R1830 operates, when its lower winding is energized over the circuit just traced and, upon operating, prepares, at RA1831, the previously traced circuit for energizing the operating magnet 1772 of the minor switch 1770. Also, the relay R1830, upon operating, initiates the cyclic operation of the three relays R1800, R1805 and R1810, in the manner explained previously. During the portion of each cycle of operation of these three relays when the relay R1805 is energized, the operating circuit for the magnet 1772 is completed. Hence, the wiper 1771 is operated one step during each cycle of operation of the three relays R1800, R1805 and R1810. The stepping operation on the part of the minor switch 1770 continues until the wiper 1771 thereof is operated to its ninth off-normal position or until the first of a series of impulses is transmitted by way of the trunk line 31 to the repeater shown in Figs. 17 and 18.

When the previously mentioned loop circuit is completed by way of the trunk line 45 to the line circuit shown in Fig. 23, this line circuit responds by causing one of the local finder-connector links provided in the exchange C to be assigned to the use of the calling line 45. More particularly, when the relay R1750 operates in the manner just explained, the line relay R2300 is energized over a circuit which may be traced as extending from ground at RA2321 by way of C2326, RA1759, C1796, the winding 1875, C1785, the resistor 1761, the lower winding of R1765, RA1755, C1787, RA1863, the winding 1874, C1775, RA1751, C2325, RA2324 and the winding of R2300 to battery. When energized over this circuit, the relay R2300 completes, at RA2301, a path including the winding of R2320 and RA2311 for applying negative battery potential to the control conductor C2321, thereby to mark the calling line 45 in the bank contacts of the finder switches having access to this line. At RA2302, the relay R2300, upon operating, completes a path extending by way of R2312 for applying ground potential to the start conductor C2328. The link distributor illustrated

in Fig. 22 responds to the application of ground potential to the start conductor C2328 in the manner explained in the preceding section by initiating the operation of the finder portion of an idle one of the finder-connector links to seize the calling line 45. If it be assumed, for example, that the link illustrated in Figs. 19 and 20 is assigned by the distributor shown in Fig. 22 to the use of the calling line 45, the manner in which the finder portion 2070 of the link operates to seize the calling line is exactly the same as set forth in the preceding section of the specification. When the calling line is seized, the control conductor C2327 thereof is grounded to complete a circuit extending by way of RA2301 and RA2311 for energizing the cut-off relay R2320. The relay R2320 now operates to complete, at RA2322, a holding circuit for itself, and to complete, at RA2323, an obvious circuit for energizing the lock-out relay R2310. At RA2321 and RA2324, the relay R2320 disconnects ground and the line terminal of the relay R2300 from the respective conductors of the line 45 causing the last-mentioned relay to restore. Upon restoring the relay R2300 opens the operating circuit for the relay R2320 and, at RA2302, disconnects the start conductor C2328 from ground. The lock-out relay R2310, upon operating, prepares a holding circuit for itself and opens, at RA2311, a further point in the operating circuit for the cut-off relay R2320.

Following the seizure of the repeater illustrated in Figs. 26 and 27, the repeater shown in Figs. 17 and 18, the line circuit of Fig. 23 and the local finder-connector link of Figs. 19 and 20, the switch train is conditioned to respond to the impulses making up the first digit dialed at the calling substation. In this regard, it is again pointed out that, when the relay R2000 embodied in the seized finder-connector link operates, it completes, at RA2004 and RA2004', the previously traced path for impressing dial tone voltage upon the talking circuit extending back to the calling substation, thereby to signal the calling subscriber that the dialing operation may be started.

Referring now more particularly to the operation of the switching selector repeater shown in Figs. 28 and 29 during impulsing, when the calling device provided at the calling substation T₄ is operated, the loop circuit extending by way of the line 59 is opened one or more times during each digit and the line relay R2820 responds by restoring during the open circuit period of each impulse. Each time the line relay R2820 restores it opens, at RA2822, the operating circuit for the hold relay R2825, but this hold relay, due to its slow-to-release characteristic, remains operated during impulsing. At the beginning of the first impulse of the first digit and when the line relay R2820 first restores, the above-mentioned circuit is completed for energizing the slow-acting relay R2840 in parallel with the relay R2850 and the operating magnet 2903 of the minor switch 2900. This circuit may be traced as extending from ground at RA2822 to RA2828, where it divides, one branch through the winding of R2840 to battery, a second branch extending by way of C2869, RA2913 and the winding of the magnet 2903 to battery, and the remaining branch extending by way of C2869, RA2913, C2870, RC2853, RA2852, and the winding of R2850 to battery. When energized over this circuit, the relay R2840 operates to complete, at RA2841, a path including the resistor 2879 for 75

shunting the two series connected windings of the relays R2830 and R2835, thereby to reduce to a low value the resistance of the pulsing circuit extending over the trunk line 45 to the repeater shown in Figs. 26 and 27. At RA2842, the relay R2840 prepares a holding circuit extending by way of RA2851 and RA2852 for the relay R2850, this holding circuit being completed in response to the operation of R2850. At RA2854, the relay R2850 disconnects the wiper 2902 of the minor switch 2900 from ground. At RA2855, the relay R2850 completes an obvious path shunting the armature RA2913 of the relay R2910, thereby to maintain the above-traced pulsing circuit complete after the relay R2910 has been caused to operate. At the end of the open circuit period of the first impulse, the line relay R2820 reoperates to open the pulsing circuit and to recomplete the operating circuit for the hold relay R2825, while at the beginning of the second impulse, the line relay again restores to recomplete the pulsing circuit and to open the operating circuit for the hold relay. Due to its slow-to-release characteristic, the relay R2840 and the relay R2850 controlled thereby remain operated during each series of impulses. During each impulse of the first digit, the operating magnet 2903 of the minor switch 2900 is energized and deenergized, and this magnet, in cooperation with its associated ratchet and pawl mechanism, responds by stepping the wiper 2902 from its home position over the contacts of the contact set 2901 at the rate of one step for each impulse. When the wiper 2902 is moved to its first off-normal position, the off-normal springs 2905 embodied in the switch 2900 are closed to complete an obvious circuit for energizing the relay R2910. The relay R2910, upon operating, opens, at RA2911, a point in the previously traced circuit for energizing the heating coil 2858 of the thermal relay 2857, thereby to arrest the operation of this thermal relay. At RA2912, the relay R2910 prepares a circuit, traced hereinafter, for energizing the relay R2920. At RA2913, the relay R2910 opens a point in the original pulsing circuit, as traced above. At RA2914, the relay R2910 opens a further point in the path for applying ground potential to the guard conductor C3055. At RA2915, the relay R2910 prepares a point in the circuit, traced hereinafter, for energizing the release magnet 2904 of the minor switch 2900. Finally, the relay R2910 prepares, at RA2916, a circuit, traced hereinafter, for impressing busy tone voltage upon the loop circuit extending to the calling substation.

At the end of the first series of impulses dialed at the calling substation T₄, the wiper 2902 of the minor switch 2900 is left standing in engagement with the contact of the set 2901 which corresponds to the number of impulses making up the dialed digit. With the wiring arrangement illustrated, a first digit of four impulses is required to cause a seized switching selector repeater to select an idle one of the local connector switches provided in the exchange C. Thus, in making the call under consideration, if the calling subscriber at the substation T₄ dials a first digit comprising four impulses, the wiper 2902 is left standing in engagement with the fourth contact of the contact set 2901 at the end of the digit. During the impulses of this digit, the line relay R2820 operates to repeat the impulses to the repeater shown in Figs. 26 and 27 by opening, at RA2821, the loop circuit

extending to this repeater once during each impulse of the series. At the end of the first digit, the line relay R2820 remains energized for a sufficient time interval to permit the relay R2840 to restore. Upon restoring, the relay R2840 opens, at RA2841, a point in the path shunting the series connected windings of R2830 and R2835 and interrupts, at RA2842, the previously traced holding circuit for the relay R2850. The relay R2850 now restores to open, at RA2851 and RA2852 a further point in its holding circuit and to open, at RA2855, a further point in the pulsing circuit extending to the operating magnet 2903 of the minor switch 2900. At RA2854, the relay R2850, upon restoring, completes a path for short-circuiting the winding of the relay R2940, this short-circuiting path extending from ground at RA2827 by way of RA2854, C2868, the wiper 2902, the fourth contact of the set 2901, RA2933, the winding of R2940, RA2944, RA2951 and C2867 back to ground at RA2827. When this short-circuiting path is completed, the relay R2940 restores to open, at RA2941, a further point in the previously traced circuit for energizing the heating element 2858 of the thermal relay 2861 and to open, at RA2945, a point in the previously traced operating circuit for the two relays R2920 and R2930. At RA2944, the relay R2940 opens a point in its holding circuit. At RA2943, the relay R2940 interrupts the holding circuit for R2960, causing the last-mentioned relay to restore. The relay R2960, upon restoring, opens, at RA2964, a point in its operating circuit, as traced above, and interrupts, at RA2962, a point in the path for applying ground potential to the control conductor C2895 of the trunk line 63. At RA2961 and RA2965, the relay R2960 opens two points in the loop circuit extending to the repeater illustrated in Figs. 26 and 27, thereby to initiate the release of this repeater, the repeater illustrated in Figs. 17 and 18, and the local connector switch provided in the exchange B and illustrated in Figs. 19 and 20, all in the manner explained hereinafter.

At RA2942, the relay R2940 completes a circuit for energizing the relay R2970, which circuit may be traced as extending by way of the grounded conductor C2867, RA2951, RA2931, RA2942, and the two series connected windings of R2970 to battery. When energized over this circuit, the relay R2970 partially operates to close the "X" contacts respectively associated with its armatures RA2973 and RA2974. At the last-mentioned contacts, a path is completed for short-circuiting the lower winding of R2970, this path extending from ground by way of the wiper 2983, RA2972, RA2973, RA2974, the lower winding of R2970, RA2942, RA2931, RA2951 and C2867 back to ground at RA2827. The completion of this path prevents the relay R2970 from fully operating. At the "X" contacts associated with RA2973, the relay R2970 completes a circuit for again energizing the operating magnet 2985 of the rotary switch 2980, this circuit extending by way of the grounded wiper 2983, RA2972, RA2973, the armature 2986 and the winding of the magnet 2985 to battery. In further explanation of the bank wiring arrangement of the rotary switch 2980, it is pointed out that the contacts of the set associated with the wiper 2983 which correspond to trunk lines, as, for example, the line 63, extending to repeaters of the character shown in Figs. 26 and 27, are all grounded so that, when the wipers of the switch 2980 are

positioned on a set of contacts terminating one of these trunk lines, the wiper 2983 is connected directly to ground. The resulting energization of the operating magnet 2985 in response to the partial operation of R2970 causes this magnet to operate to open, at RA2986, a point in its own operating circuit and to prepare its associated ratchet and pawl mechanism to step the wipers of the switch 2980 one step. This stepping operation occurs when the magnet 2985 is deenergized and restores its armature 2986. If, at the end of this first step, the wipers are still positioned on a set of contacts terminating a trunk line extending to another of the repeaters, ground potential is retained upon the wiper 2983 so that the operating circuit for the magnet 2985 is recompleted and the wipers are stepped a second step. The stepping operation of the wipers embodied in the switch 2980 continues until such time as the wiper 2983 is moved into engagement with a contact terminating the control conductor of a trunk line extending to an idle one of the local connector switches. If, for example, the local connector switch shown in Fig. 33 is the first available idle switch of this character, the wipers 2981 to 2984, inclusive, are only stepped a single step, at which time ground potential is removed from the wiper 2983 and no further circuit is available for energizing the operating magnet 2985 of the switch 2980. When ground potential is removed from the wiper 2983, the path short-circuiting the lower winding of the relay R2970 is interrupted and the two windings of this relay are energized in series over the previously traced operating circuit for this relay. The relay R2970 now completes its operation to open, at RA2972 and its associated resting contact, a further point in the above-traced path for short-circuiting its lower winding and a point in the operating circuit for the magnet 2985. At RA2972 and its associated working contact, the relay R2970 completes a path extending by way of the wiper 2983 for impressing ground potential upon the control conductor C2988 of the trunk line extending to the local connector switch shown in Fig. 33, thereby to mark this local connector switch as busy in the bank contacts of the other switching selector repeaters located in the exchange C. At RA2971 and RA2975, the relay R2970 completes a loop circuit extending by way of the trunk line conductors C2987 and C2990 to the selected local connector switch. More particularly, when the relay R2970 fully operates, the line relay R3310 embodied in the local connector switch of Fig. 33 is energized over a circuit which may be traced as extending from ground at the upper terminal of the lower winding of R3310 by way of this winding, RA3302, C2990, the wiper 2984, RA2975, RA2952, C2874, the winding of R2835, the upper winding of R2830, RA2821, C2865, RA2971, the wiper 2981, C2987, RA3301 and the upper winding of R3310 to battery. The line relay R3310 operates, when energized over the above-traced loop circuit and, upon operating, completes at RA3311 an obvious circuit for energizing the slow-acting hold relay R3315. At RA3312, the relay R3310 opens a point in the circuit, traced hereinafter, for energizing the operating magnet 3396 embodied in the rotary switch 3390. At RA3313, the relay R3310 prepares an incomplete pulsing circuit, traced hereinafter, for impressing pulses of negative battery potential upon the positive line conductor of a selected line of the multiplex type. The hold relay R3315, upon op-

erating completes, at RA3316, an obvious circuit for energizing the relay R3320 and prepares, at RA3317, a point in the above-mentioned circuit for energizing the operating magnet 3396 of the rotary switch 3390. The relay R3320, upon operating, completes, at RA3322, an obvious multiple path for maintaining ground potential upon the control conductor C2988 of the trunk line extending to the local connector switch shown in Fig. 33 and prepares, at RA3324, a point in the common portion of the locking circuits, traced hereinafter, for the relays R3346, R3350, R3370 and R3388. At RA3324 and its associated resting contact, the relay R3320 interrupts one multiple path for maintaining ground upon the all-switch-busy conductor C2989. At RA3323, the relay R3320 prepares a circuit, traced hereinafter, for energizing the slow-acting relay R3330. Finally, the relay R3320, upon operating, opens, at RA3325, a point in a circuit, traced hereinafter, for energizing the relays R3333 and R3346. Following the operation of the relay R3320, the local connector switch shown in Fig. 33 is conditioned to respond to the impulses of the second digit dialed at the calling substation T₄.

Before describing the operation of the switching selector repeater shown in Figs. 28 and 29 and the local connector switch illustrated in Fig. 33 in response to the impulses of the second digit dialed at the calling substation, it is pointed out that in the event all of the local connector switches provided in the exchange C are busy at the time the trunk hunting operation of the rotary switch 2980 is initiated, this switch continues to operate until the wiper 2983 is positioned upon its associated first contact. Thus, with all of the local connector switches busy, ground potential is encountered by this wiper as it traverses the contacts terminating the respective control conductors of the trunk lines individually extending to the local connector switches. Also, when all of the local connector switches are busy, the all-switch-busy conductor C2989 is open circuited, whereas, when any one of the switches is idle, this conductor has ground potential impressed thereon. With this arrangement, when the wiper 2983 is operated into engagement with its first contact, further energization of the operating magnet 2985 embodied in the switch 2980 is prevented and the switching relay R2970 is caused to complete its operation in the manner explained above. Upon operating, the switching relay R2970 completes the above-mentioned circuit for returning the usual busy tone signal to the calling subscriber. The path traversed by the busy tone current extends from the ungrounded terminal of the busy tone source by way of the condenser 2966, RA2916, the first contact of the set associated with the wiper 2984, the wiper 2984, RA2975 and RA2952 to the line conductor C2874, and over the calling loop circuit to the receiver provided at the calling substation. When this path is completed the calling subscriber receives the usual busy tone signal. Since the first and second contact sets of the bank contact field embodied in the switch 2980 are reserved for control purposes, it will be apparent that the dialing of additional digits at a time when all of the local connector switches are busy is without any effect whatever, the busy tone signal persisting after the dialing operation is completed to inform the calling subscriber that the desired connection cannot be obtained. The manner in which the partially completed connection is re-

leased when the calling subscriber hangs up upon receiving busy tone is substantially similar to the release of the connection as described hereinafter.

Continuing now with the operation of the local connector switch in response to the impulses of the second and third digits dialed at the calling substation T₄, the line relay R2820, embodied in the operated switching selector repeater, functions in the manner explained above to open and close the contact springs associated with RA2821 during each impulse of each digit, thereby to repeat the impulses to the local connector switch shown in Fig. 33. Since the relay R2910 is now operated, the relay R2850 is prevented from operating and, thus, the impulses of the digits following the first digit are not transmitted to the operating magnet 2903 of the minor switch 2900. The line relay R3310 embodied in the local connector switch follows the operation of the line relay R2820 and repeats the impulses to the operating magnet 3396 of the rotary switch 3390. More particularly, during the open circuit period of each impulse, the relay R3310 restores to complete, at RA3312, the above-mentioned circuit for energizing the operating magnet 3396. This circuit extends from ground at RA3312 by way of RA3317, RA3362, RA3386 and the winding of the magnet 3396 to battery. At the beginning of the first impulse of the second digit dialed at the calling substation and when the line relay R3310 restores, a circuit is also completed for energizing the winding of the relay R3330 in parallel with the upper winding of the relay R3340, this circuit extending from ground at RA3311 by way of RA3323, RA3353, to RA3335, where it divides, one branch extending through the winding of R3330 to battery, and the other branch extending through the upper winding of R3340 to battery. The relay R3330 now operates to complete, at RA3331, an obvious circuit for energizing the lower winding of the relay R3340. At RA3332, the relay R3330 completes a path extending by way of RA3324 for applying ground potential to the test wiper 3394 of the rotary switch 3390. The relay R3340, upon operating, completes, at RA3344, an obvious multiple holding circuit for itself and the relay R3330; prepares, at RA3341 and RA3342, a circuit, traced hereinafter, for energizing the busy test relay R3350; and opens, at RA3345, a point in one path for impressing negative battery potential upon the positive side of a selected line of the multiplex type. When ground potential is impressed upon the test wiper 3394 of the switch 3390, a circuit is completed for energizing the relays R3333 and R3346, this circuit extending by way of the grounded test wiper 3394 and the home contact engaged by this test wiper, RC3338, RA3337, the winding of R3333 and the upper winding of R3346 to battery. When energized over this circuit, the relay R3333 operates to complete, at RA3336 and RA3337, a holding circuit for itself, which circuit may be traced as extending from ground at RA3324 by way of RA3332, RA3336, RA3337, the winding of R3333 and the upper winding of R3346 to battery. At RA3334, the relay R3333, upon operating, opens a point in the above-mentioned circuit for energizing the busy test relay R3350. At RA3335, the relay R3333 opens a point in the original operating circuit for the relays R3330 and R3340. At RA3339, the relay R3333 prepares a circuit, traced hereinafter, for ener-

gizing the operating magnet 3396 of the rotary switch 3390 by way of the circuit interrupting contacts associated with the armature 3397. The relay R3346 operates when its upper winding is energized in series with the winding of the relay R3333 and, upon operating, completes, at RA3347, a holding circuit for itself, which holding circuit extends from ground at RA3324 by way of RA3347 and the lower winding of R3346 to battery. At RA3348, the relay R3346 prepares a point in the operating circuit for the line switching relay R3380. At the end of the open circuit period of the first impulse when the line relay R3310 reoperates to interrupt the above-traced circuit for energizing the magnet 3396, this magnet, in cooperation with its associated ratchet and pawl mechanism, steps the wipers of the switch 3390 one step from the home position or to the first off-normal position. Similarly, during each succeeding impulse of the second series of impulses dialed at the calling substation, the magnet 3396 is energized and deenergized. Thus, the wipers of the switch 3390 are moved over the contacts of their respective associated sets at the rate of one step for each impulse. The number of impulses making up the second digit dialed at the calling substation is dependent upon which of three groups of lines includes the called line 60. In this regard, it is pointed out that the bank wiring arrangement of the rotary switch 3390 corresponds to the wiring arrangement of the rotary switch 3250 embodied in the incoming connector switch shown in Figs. 31 and 32 in that the lines terminating in the bank contacts of the switch 3390 are divided into three groups. More particularly, the lines of the first group are terminated at the contact sets numbered from 3 to 8, inclusive, of the contact field embodied in the rotary switch 3390, and the ninth set of contacts is reserved as the preliminary or starting position for the selection of lines in the second group. The lines of the second group are terminated at the contacts sets numbered from 10 to 19, inclusive, in the rotary switch contact field, and the twentieth contact set is reserved as the preliminary or starting position for the selection of lines in the third group. The lines of the third group are terminated at the contacts numbered from 21 to 25, inclusive, the twenty-fifth contact set also being used as the home position of the switch. With the bank wiring arrangement just described, it will be apparent that, to select a line in the first group, it is necessary to transmit to the local connector switch a first digit of two impulses followed by a second digit corresponding to the particular desired line of the group. If the desired line is in the second group, a first series of from three to nine impulses, followed by a second series of from one to ten impulses, must be transmitted to the local connector switch for the purpose of causing the wipers of the rotary switch 3390 to be operated into engagement with the contacts terminating the desired line. In order to select a line in the third group of lines, a first series of ten impulses, followed by a second series of from one to five impulses, depending upon the line being called, are required to cause the desired line selection to be performed by the local connector switch. In the present case, wherein the called line 60 is the third line in the first group of lines, the second and third digits dialed at the calling substation necessarily comprise two and three impulses, respectively,

so that, at the end of the second digit, the wipers 3391 to 3395, inclusive, are positioned in engagement with their respective associated second contacts. Shortly following the end of this digit and with the line relay R3310 in its operated position, the relay R3330 restores to open the holding circuit for R3340, causing the latter relay to restore. Since the test wiper 3394 is now standing in engagement with its associated second contact, and this contact is not connected to ground, the restoration of the relay R3330 also results in the deenergization of R3333, causing the last-mentioned relay to restore. The local connector switch illustrated in Fig. 33 is now conditioned to respond to the impulses of the third digit dialed at the calling substation T4. The line relay R3310 follows the impulses of the third digit and the two relays R3330 and R3340 reoperate at the beginning of the digit, all in the manner explained previously. During each impulse of the third digit, the operating magnet 3396 of the rotary switch 3390 is energized and deenergized through the completion and interruption of the previously traced pulsing circuit and, in cooperation with its associated ratchet and pawl mechanism, steps the wipers of the switch 3390 over their respective associated contacts until, at the end of the digit, the wipers are standing in engagement with the contacts terminating the conductors of the desired line. During this third series of impulses, the relay R3330, due to its slow-to-release characteristic, remains operated to maintain the holding circuit for the relay R3340 completed. With the relay R3340 operated, the above-mentioned test circuit, extending through the winding of the busy test relay R3350, is prepared. When the wipers of the switch 3390 are moved into engagement with the contacts terminating the conductors of the called line 60, the test circuit, mentioned above, is completed, this test circuit extending by way of the control conductor C3482, the wiper 3392, RA3334, RA3341, RA3342 and the winding of R3350 to battery. If the called line is busy, such that ground potential is present upon the control conductor C3482, the busy test relay R3350 is energized over the test circuit just traced and operates to open, at RA3352 and its associated resting contact, a point in the circuit, traced hereinafter, for energizing the upper winding of the line switching relay R3380. At RA3352 and its associated working contact, the relay R3350 prepares a holding circuit for itself, which holding circuit is completed shortly following the end of the third digit dialed at the calling substation and in response to the sequential restoration of the two relays R3330 and R3340. This holding circuit may be traced as extending from ground at RA3324 by way of RA3352, RC3343, RA3342 and the winding of R3350 to battery. The relay R3350 also opens, at RA3353, a point in the above-traced operating circuit for the two relays R3330 and R3340. At RA3355, the relay R3350 completes a circuit for projecting busy tone current over the calling loop circuit to energize the receiver provided at the calling substation. The path traversed by this current may be traced as extending from the ungrounded terminal of the busy tone current source by way of the condenser 3398, RA3388 and RA3355, and over the calling loop circuit to the receiver provided at the calling substation. When this path is completed, the usual busy tone signal is received by the calling subscriber. Upon receiving busy tone, the calling subscriber may initiate

the release of the connection by hanging up to open the calling loop circuit. The manner in which the operated switching selector repeater and the operated local connector switch are released when the calling subscriber hangs up following the selection of a busy line is explained hereinafter.

As explained previously if the called line 60 is idle at the time it is selected by the local connector switch shown in Fig. 33, battery potential is present upon the control conductor C3482 thereof. Accordingly, the busy test relay R3350 is not energized over the test circuit as traced above. Shortly following the end of the third digit dialed at the calling substation and when the two relays R3330 and R3340 restore in the manner explained previously, the above-mentioned circuit is completed for energizing the upper winding of the line switching relay R3380, this circuit extending from ground at RA3324 by way of RA3348, RA3352, the upper winding of R3380, RA3341, RA3334, the wiper 3392, the control conductor C3482, RA3422 and the winding of the cut-off relay R3440 to battery. When energized over this circuit, the cut-off relay R3440 operates to complete, at RA3445, the operating circuit for the lockout relay R3430 and to prepare, at RA3444, a path for applying ground potential to the control conductor C3487. At its armatures RA3441 and RA3446, the cut-off relay R3440, upon operating, disconnects the line terminals of the relay R3400 from the conductors of the line 60, thereby to clear the called line 60 of the impedance of the line relay windings. The lockout relay R3430, upon operating, opens at RA3431, a point in the incomplete path for applying negative battery potential to the control conductor C3487 and opens, at RA3432, a point in the path for applying ground potential to the distributor start conductor C3433.

The switching relay R3380 operates, when its upper winding is energized in series with the cut-off relay R3440, and during its operation, first completes, at the "X" contacts associated with RA3385, a circuit for energizing its lower winding, this circuit extending from ground at RA3324 by way of RA3385 and the lower winding of R3380 to battery. At RA3388, the relay R3380 opens a point in the circuit, traced previously, for projecting busy tone current over the calling loop circuit. At RA3386, the relay R3380 opens a point in the above-traced circuit for energizing the operating magnet 3396 of the switch 3390. At RA3384, the relay R3380 prepares a circuit, traced hereinafter, for energizing the relay R3360, this circuit not being completed in the present case since the extra control wiper 3393 stands in engagement with an open-circuited contact. At RA3383, the relay R3380 completes an obvious path for impressing ground potential directly upon the control conductor C3482, thereby to complete a holding circuit for the cut-off relay R3440 embodied in the line circuit associated with the called line and to mark the called line as busy in the bank contacts of the other connector switches having access thereto. When this path is completed the upper winding of the relay R3380 is short-circuited, thereby to render this relay slightly slow to release. At RA3381 and RA3387, the relay R3380 prepares two further points in the talking circuit ultimately to be completed between the calling and called substations and, in so doing, completes a circuit for projecting ringing current over the called line to energize the signal device 3460 pro-

vided at the called substation T₅. More particularly, the path traversed by the ringing current may be traced as extending from one terminal of the ringing current source provided in the exchange C, by way of the exchange battery, the winding of the slow-acting ring cut-off relay R3365, RA3361, RA3371, RA3381, the wiper 3391, C3481, RA3451, the pulsing springs of the calling device 3493, the switch springs 3456 and 3455, the condenser 3491 and the winding of the signal device 3460 to the opposite terminal of the ringing current source. A portion of the ringing current is also caused to traverse the loop circuit extending to the calling substation, whereby the usual ring-back tone signal is reproduced by the receiver provided at this substation. More particularly, a portion of the ringing current flows over a circuit which may be traced as extending from the ungrounded terminal of the ringing current source by way of the exchange battery, the winding of R3365, RA3361, RA3371, RA3381, RA3382, the condenser 3399 and the calling loop circuit to energize the receiver provided at the calling substation.

The operation of the signal device 3460 provided at the called substation T₅ serves to signal the called subscriber that his substation is being called. When the called subscriber removes the receiver provided at the called substation from its associated supporting hook or cradle, the hook switch arm 3457 is moved into engagement with the associated spring 3456, and the springs 3455 and 3456 are opened to interrupt the above-traced circuit for energizing the signal device 3460. When the spring 3456 is engaged by the switch hook arm 3457, a circuit is completed for energizing the lockout relay R3470 in series with the ring cut-off relay R3365 embodied in the local connector switch. This circuit may be traced as extending from ground at RC3473, by way of RA3472, the winding of R3470, the transmitter 3459, the receiver 3458, the switch hook arm 3457, the contact spring 3456, the pulsing springs embodied in the calling device 3493, RA3451, C3481, the wiper 3491, RA3381, RA3371, RA3361 and the winding of R3365 to battery. When energized over this circuit, the slow-to-release lockout relay R3470 operates to complete an alternative circuit for energizing its own winding in series with the winding of R3365, this alternative circuit being substantially similar to that just traced but extending to ground at RA3363 over a path including RA3471, C3483, the wiper 3395, RA3387 and RA3375. The slow-acting ring cut-off relay R3365 operates, after an interval to complete, at RA3366, an obvious circuit for energizing the relay R3370, which latter relay operates, in turn, to complete, at RA3374 an obvious holding circuit for itself. At RA3373, the relay R3370 opens a point in the operating circuit for the relay R3360. At RA3371 and its associated resting contact, the relay R3370 opens a point in the above-traced circuit for energizing the signal device 3460 provided at the called substation T₅ and also a point in the circuit, traced previously, for projecting ring-back tone current by way of the calling loop circuit to energize the receiver provided at the calling substation T₄. At RA3371 and RA3375 and their respective associated resting contacts, the relay R3370 opens two points in the above-traced alternative circuit for energizing the winding of R3365 in series with the winding of R3470. At these same armatures and their respective associated working contacts, the relay R3370 connects the calling loop

circuit to the loop extending to the called substation, thereby to complete the desired talking connection between the two substations and, in so doing, completes a second alternative circuit for energizing the winding of R3470 in series with the two windings of the battery reversing relay R3300. The last-mentioned alternative circuit may be traced as extending from ground at the upper terminal of the lower winding of R3300 by way of this winding, RA3375, RA3387, the wiper 3395, C3483, RA3471, RA3472, the winding of R3470, the transmitter 3459, the receiver 3458, the hook switch arm 3457, the contact spring 3456, the pulsing springs of the calling device 3493, RA3451, C3481, the wiper 3391, RA3381, RA3371 and the upper winding of R3300 to battery. The relay R3470 remains operated, when energized over this circuit, and, in its operated position, effectively locks the apparatus provided at the substation T₆ out of service to guard the established connection against intrusion resulting from the initiation of a call at the substation T₆. The battery reversing relay R3300 operates, when its two windings are energized in series with the lockout relay R3470 and, upon operating, attracts its two armatures RA3301 and RA3302 to reverse battery back over the trunk line conductors C2887 and C2890 in the usual manner. The effect of this battery reversal is to reverse the direction of current flow through the upper winding of the relay R2830, so that the two windings of this relay are cumulatively energized. The relay R2830 now partially operates to complete, at the "X" contacts associated with RA2831, an obvious path for short-circuiting the resistor 2880. The resulting increase in the current traversing the lower winding of R2830 causes this relay to complete its operation, whereby an obvious path is completed, at RA2832, for applying ground potential to the metering conductor C2878 extending to the line circuit 55. When ground potential is applied to the conductor C2878, the metering device, not shown, but embodied in the line circuit 55, is caused to operate in the usual manner to register the call. Following the operation of the relay R2830 in the manner just explained, no further operation of the control apparatus embodied in the switching selector repeater shown in Figs. 28 and 29 and the local connector switch shown in Fig. 33 occurs until the connection is released.

Before describing the release of the established connection and in order to explain fully the operation of the local connector switch illustrated in Fig. 33, the manner in which this switch operates to select a line in each of the second and third groups of lines terminating in the bank contacts of the switch 3390, and selectively to signal the two substations associated with a line of the duplex type will be briefly considered. In order that the signal devices 3460 and 3480 respectively provided at the substations T₅ and T₆ may selectively be energized, the line conductors of the line 60 are reversely connected to the contacts forming two contact sets in the bank contact field of the switch 3390, all in the manner described above with reference to the bank wiring arrangement of the incoming connector switch shown in Figs. 31 and 32. More particularly, in one of the two contact sets the line conductor C3481 is terminated in the contact level associated with the wiper 3391 and in the other contact set it is terminated in the level of contacts associated with the wiper 3395. Conversely, the opposite line conductor C3483 is, in the first

case, terminated at a contact in the level associated with the wiper 3395 and, in the second case, at a contact in the level associated with the wiper 3391. By virtue of this arrangement, it is possible to assign different directory numbers to the two substations T₅ and T₆, the two directory numbers having the same group select digits but different units digits. With this arrangement, if the substation T₆ is called rather than the substation T₅, the wiper 3391 is moved into engagement with a contact terminating the line conductor C3483 rather than the line conductor C3481. Hence, during the ringing operation, ringing current is projected over the line conductor C3483 to energize the signal device 3480 provided at the substation T₆, and the signal device 3460 provided at the substation T₅ does not operate. Also, when the call is answered at the substation T₆, the lockout relay R3450 is energized in series with the ring cut-off relay R3365, thereby effectively to guard the connection against intrusion resulting from the initiation of a call at the substation T₅. In this regard, it is pointed out that the operating and alternative holding circuits for the lockout relay R3450 commonly include the line conductor C3483, RA3471, the pulsing springs of the calling device 3494, the switch spring 3476, the hook switch arm 3477, the receiver 3478, the transmitter 3479, the winding of R3450 and the armature RA3452. Also, the operating circuit for the lockout relay R3450 extends from ground at RC3453, whereas each of the two alternative holding circuits for this relay includes a return path comprising RA3451 and the opposite line conductor C3481. Aside from the differences noted, the mode of completing a connection to the substation T₆ when the line 60 is seized by the local connector switch shown in Fig. 33 is exactly the same as set forth above with reference to the connection routed to the substation T₅.

As indicated previously, if the connection routed to the local connector switch illustrated in Fig. 33 is to be extended to a line included in the second group of lines terminating in the bank contact field of the rotary switch 3390, the second digit dialed at the called substation T₄ must comprise at least three impulses. Assuming that a second digit of three impulses is dialed, at the conclusion of the digit, the wipers 3391 to 3395 are left standing in engagement with their respective associated third contacts. With the test wiper 3394 occupying this position, an alternative holding circuit is completed for the relay R3333, this circuit extending from ground, as connected to the multiplied third to eighth contacts of the set associated with the test wiper 3394, by way of this wiper, RA3336, RA3337, and the winding of R3333 to battery. With the relay R3333 operated and when the relay R3333 restores shortly following the end of the digit in the manner explained previously, an alternative circuit is completed for energizing the operating magnet 3396 of the rotary switch 3390, this alternative circuit extending by way of the grounded test wiper 3394, RA3332, RA3339, the armature 3397 and the winding of the magnet 3396 to battery. Due to the circuit interrupting action of the contact springs associated with the armature 3397, the magnet 3396 operates, buzzer fashion, to drive the wipers of the switch 3390 over the contacts of their respective associated contact levels until the test wiper 3394 is moved out of engagement with its associated eighth contact and into engagement with its associated ninth contact. The ninth contact of the level associated with the wiper 3394

represents the preliminary or starting position of the switch for the selection of lines in the second group of lines terminating at the local connector and is left unwired so that when engaged by the wiper 3394 no further circuit is available for energizing the rotary switch operating magnet 3396 and the operation of the switch is arrested. When ground potential is removed from the wiper 3394, the relay R3333 is deenergized and restores to open, at RA3336 and RA3337, a further point in its holding circuit and to reprepare, at RA3337 and RC3338, its operating circuit, as traced above. At RA3339, the relay R3333 opens a further point in the above-traced alternative operating circuit for the rotary switch operating magnet 3396. At RA3335, the relay R3333 prepares the operating circuit for the two relays R3330 and R3340. Finally, the relay R3333, upon restoring, prepares, at RA3334, a point in the common portion of the respective operating circuits for the busy test relay R3350 and the line switching relay R3380. Following the operation of the switch wipers 3391 to 3395, inclusive, to their respective ninth off-normal positions and the restoration of the relay R3333, the connector switch illustrated in Fig. 33 is conditioned to respond to the third series of impulses dialed at the calling substation T₄. From this point on, the mode of operation of the indicated connector switch to select the desired line of the second group and to complete a talking circuit to the called substation is exactly the same as set forth above with reference to the connection extended to the substation T₅.

If the call, initiated at the substation T₄ and routed to the local connector switch shown in Fig. 33 in the manner explained previously, is to be extended to a line in the third group of lines terminating in the bank contacts of the rotary switch 3390, a second digit of ten impulses is dialed at the calling substation. The indicated local connector switch responds to the ten impulses of this digit by operating the wipers 3391 to 3395, inclusive, to their respective tenth off-normal positions. With the test wiper 3394 occupying its tenth off-normal position, the above-traced alternative holding circuit for the relay R3333 is completed and the above-traced alternative circuit for energizing the rotary switch operating magnet 3396 is prepared. The last-mentioned circuit is completed in response to the restoration of the relay R3330 shortly following the end of the second digit. In this case, the operating magnet 3396 operates, buzzer fashion, to drive the wipers of the switch 3390 over the contacts of their respective associated contact levels until they occupy their respective nineteenth off-normal position. When the test wiper 3394 is moved to this position, the alternative operating circuit, as traced above, for the magnet 3396 is opened and the relay R3333 is deenergized and restores. Thus, the control apparatus embodied in the connector switch of Fig. 33 is conditioned to respond to the third series of impulses dialed at the calling substation. The manner in which the connector switch responds to the impulses of the third series to select a line in the third group is exactly the same as set forth above with reference to the selection of the line 60 included in the first group of lines terminating in the bank contacts of the rotary switch 3390.

As pointed out previously, if the call initiated at the substation T₄ and routed to the local connector switch shown in Fig. 3 is to be extended to a substation associated with a subscriber's line 75

of the multiplex type, a fourth series of impulses must be dialed at the calling substation for the purpose of causing the station selecting apparatus associated with the called line to operate and select the desired substation on the line. In order to condition the relay equipment embodied in the local connector switch to transmit the additional series of impulses to the line selecting apparatus, each of the contacts in the set associated with the extra control wiper 3393 which corresponds to a line of the multiplex type is connected to ground. Hence, if the local connector switch is caused to select a line of the multiplex type, in the manner explained immediately above and this line tests idle so that the line switching relay R3380 is caused to operate, a circuit is completed for energizing the relay R3360, this circuit extending by way of the grounded wiper 3393, RA3384, RA3373, and the winding of R3360 to battery. Upon operating, the relay R3360 opens, at RA3361, a point in the above-traced circuit for projecting ringing current by way of the selected called line and interrupts, at RA3362, a point in the previously traced circuit for energizing the rotary switch operating magnet 3396 in accordance with the impulses dialed at the calling substation. At RA3363 and its associated working contact, the relay R3360, upon operating, completes the previously mentioned path for impressing negative battery potential upon the positive side of the selected line, which path may be traced as extending from the negative terminal of the exchange battery provided in the exchange C by way of the resistor 3312', RA3313, RA3363, RA3375, RA3387 and the wiper 3395 to the positive line conductor of the selected called line. The switching relay R3380, upon operating, completes, at RA3383, the above-described path for impressing ground potential upon the control conductor of the selected multiplex line. When ground potential is applied to this control conductor the station selecting apparatus associated with the called line is conditioned to respond to pulses of negative battery potential transmitted by way of the positive line conductor of the called line. Following the operation of the relay R3360, the control apparatus embodied in the local connector switch of Fig. 33 is conditioned to respond to the fourth series of impulses dialed at the calling substation T₄. At the beginning of the first impulse of this fourth series of impulses, the line relay R3310 restores to re-complete, at RA3311, the previously traced operating circuit for the two relays R3330 and R3340, causing both of these relays to operate. Upon operating, the relay R3340 completes an alternative circuit for energizing the busy test relay R3350, this circuit extending from ground at RA3383 by way of RA3334, RA3341, RA3342 and the winding of R3350 to battery. The relay R3350 now operates to prepare, at RA3352, a holding circuit for itself; to prepare, at RA3354, an alternative path for impressing negative battery potential upon the positive line conductor of the selected called line; to open, at RA3353, a point in the original operating circuit for the two relays R3330 and R3340; and to complete, at RA3351, the previously traced circuit for projecting ringing current by way of the negative side of the selected called line. The connection of the ringing current source to the negative line conductor of the selected called line is effective to cause the usual ring-back tone signal to be transmitted back over the calling loop circuit to inform the calling subscriber that the called sub-

station is being signaled, and following the selection of the called substation, to energize the signal device provided at the called substation.

During the open circuit period of each impulse of the fourth digit dialed at the called substation, the line relay **R3310** restores to open, at RA3313, the above-traced path for impressing negative battery potential upon the positive line conductor of the selected called line. Thus, a series of battery pulses corresponding to the impulses of the dialed digit is transmitted by way of the positive line conductor of the called line to the station selecting apparatus associated with this line. The station selecting apparatus responds to the negative battery pulses by selecting the particular substation desired by the calling party, and by connecting the substation apparatus provided at the desired substation to the line conductors of the called line in the usual manner. At the end of the fourth series of impulses, the line relay **R3310** is held energized and the two relays **R3330** and **R3340** are caused to restore in the manner explained previously. Upon restoring, the relay **R3340** completes the previously traced holding circuit for the busy test relay **R3350** and completes, at RA3345, the above-mentioned alternative path for impressing negative battery potential upon the positive conductor of the selected called line. When the call is answered at the called substation associated with the called line, ground potential is impressed upon the negative line conductor thereof to complete a circuit extending by way of the wiper **3391**, **RA3381**, **RA3371**, **RA3351** and the winding of **R3365** for energizing the ring cut-off relay **R3365**. This relay, upon operating, completes the operating circuit for **R3370**, which latter relay now operates to complete a holding circuit for itself and to interrupt, at RA3373, the operating circuit for the relay **R3360**. At **RA3371** and its associated resting contact, the relay **R3370** interrupts the above-traced path for projecting ring-back tone current over the calling loop circuit to the calling substation and in so doing opens a point in the above-traced operating circuit for the relay **R3365**. Thus, the two relays **R3360** and **R3365** are caused to restore. At **RA3375** and its associated resting contact, the relay **R3370** opens a point in the above-traced path for impressing negative battery potential upon the positive line conductor of the selected called line. At **RA3371** and **RA3375** and their respective associated working contacts, the relay **R3370** completes the loop circuit to the called substation, thereby fully to establish the desired talking connection between the calling and called substations. When the loop circuit extending to the called substation is completed, the battery reversing relay **R3300** is energized thereover and operates to reverse battery back over the loop extending to the switching selector repeater shown in Figs. 28 and 29. The relay **R2830** responds to this battery reversal, in the manner previously explained, by operating to complete the circuit for energizing the metering device associated with the calling line **59**. Following the operation of the relay **R3370** and the resulting restoration of the two relays **R3360** and **R3365**, no further operation of the apparatus embodied in the local connector switch shown in Fig. 33 occurs until the connection is released.

The release of a connection routed by way of the switching selector repeater shown in Figs. 28 and 29 and the local connector switch shown in Fig. 33 to a substation associated with a line

terminating in the bank contacts of the rotary connector switch **3390** is entirely under the control of a calling subscriber. Thus, considering the connection routed to the substation **Ts** associated with the line **60**, by way of example, when the called subscriber at this substation hangs up, the hook switch arm **3457** is disengaged from the associated contact spring **3456** to open a point in the previously traced loop circuit over which the winding of the lockout relay **R3470** is being held energized in series with the two windings of the battery reversing relay **R3300**. The substation lockout relay **R3470** now restores to reconnect the apparatus provided at the substation **Ts** for use in communicating over the line **60**. The battery reversing relay **R3300** also restores to reverse the direction of current flow through the upper winding of the relay **R2830**. The two windings of the relay **R2830** are now differentially energized and this relay restores to open, at RA2832, the previously traced path for impressing ground potential upon the metering conductor **C2878**.

When the calling subscriber at the substation **Ts** hangs up to open the calling loop circuit, the line relay **R2820** restores to interrupt, at RA2822, the operating circuit for the hold relay **R2825** and to interrupt, at RA2821, the loop circuit extending to the operated local connector switch shown in Fig. 33. At RA2822 and its associated resting contact, the relay **R2820** momentarily re-completes the previously traced operating circuit for the relay **R2840** but the resulting operation of the last-mentioned relay is without effect at this time. When the hold relay **R2825** restores, shortly following the restoration of the relay **R2820**, it opens, at RA2828, the operating circuit for the relay **R2840** and interrupts, at RA2826, the holding circuit for the relay **R2810**. At RA2826, the relay **R2825** also opens a point in the path, traced previously, by way of which ground potential is impressed upon the control conductor **C2878** of the calling line **59**. The removal of ground potential from this control conductor results in the release of the line circuit **55** associated with the calling line **59** in the usual manner. At RA2827, the relay **R2825**, upon restoring, removes ground potential from the release conductor **C2867**, thereby to interrupt the respective holding circuits for the operated relays **R2920**, **R2930** and **R2940**, causing all of these relays to restore. When ground potential is removed from the conductor **C2867** the lower winding of the back bridge relay **R2830** is deenergized in an obvious manner. At RA2829, the relay **R2825** completes the previously mentioned circuit for energizing the release magnet **2904** of the minor switch **2900**, this circuit extending from ground by way of RA2829, **C2873**, **RA2915** and the winding of the magnet **2904** to battery. When energized over this circuit, the release magnet **2904** operates to cause the switch wiper **2902** of the minor switch **2900** to be returned to its normal position in the usual manner. When the wiper **2902** is restored to normal, the off-normal springs **2905** are opened to interrupt the operating circuit for the relay **R2910**, causing this relay to restore to complete, at RA2914, the previously traced path for impressing ground potential upon the guard conductor **C3055** extending from the distributor of Fig. 30 to the switching selector repeater shown in Figs. 28 and 29. The application of ground potential to this guard conductor serves to mark the switching selector repeater as idle in the distributor shown in Fig. 30. At RA2915 the

relay R2910, upon restoring, opens the above-traced circuit for energizing the release magnet 2904. Following the restoration of the relay R2910, the apparatus embodied in the switching selector repeater shown in Figs. 28 and 29 is fully released and the calling line 59 is marked as idle in the bank contacts of the connector switches to which this line extends.

When the loop circuit extending to the local connector switch shown in Fig. 33 is interrupted, the line relay R3310 restores to open, at RA3311, the operating circuit for the slow-to-release hold relay R3315. At RA3311, the operating circuit for the two relays R3330 and R3340 is momentarily recompleted, but the resulting operation of these relays is without effect at this time. The relay R3315 restores, after an interval, to open, at RA3316, the operating circuit for the relay R3320. When the relay R3320 falls back, it opens, at RA3322, a point in the path for applying ground potential to the control conductor C2988, thereby to mark the switch shown in Fig. 33 as idle in the bank contacts of the switching selector repeaters having access thereto. At RA3324, the relay R3320 completes one of the above-mentioned multiple paths for impressing ground potential upon the all-switch-busy conductor C2989. At RA3324 and its associated working contact, the relay R3320, upon restoring, opens a point in the common portion of the respective holding circuits for the relays R3333, R3346, R3350, R3370 and R3380, causing the operated ones of these relays to restore. At RA3323 and its associated working contact, the relay R3320 opens a point in the operating circuit for the two relays R3330 and R3340, causing these relays to restore, if operated. At RA3325, the relay R3320, upon restoring, completes an alternative circuit for energizing the relay R3333, this alternative circuit extending by way of the grounded test wiper 3394, RA3332, RA3325 and the winding of R3333 to battery. When energized over this circuit, the relay R3333 operates to complete, at RA3336 and RA3337, the previously traced holding circuit for itself and to complete a circuit for causing the rotary switch operating magnet 3396 to return the wipers of the rotary switch 3390 to their respective normal or home positions.

In this regard, it will be recalled that the contacts numbered from 3 to 8, inclusive, 10 to 19, inclusive, and 21 to 24, inclusive, of the level associated with the test wiper 3394 are all multiplied together and connected to ground. Also, with the two relays R3310 and R3320 restored, a path is completed for impressing ground potential upon the third, ninth and twentieth contacts of the contact level associated with the test wiper 3394. This path may be traced as extending from ground at RA3311 by way of RA3323 to each of the three contacts noted. Thus, all of the contacts in the level associated with the test wiper 3394, with the exception of the first and twenty-fifth contacts, have ground potential impressed thereon. Hence, the circuit for energizing the magnet 3396 may be traced as extending by way of the grounded wiper 3394, RA3332, RA3339, the armature 3397 and the winding of the magnet 3396 to battery. Due to the circuit interrupting action of the springs associated with the armature 3397, the magnet 3396 operates, buzzer fashion, to drive the wipers of the switch 3390 over the contacts of their respective associated contact levels until the home position thereof is reached. More particularly, when the test wiper 3394 is driven to its twenty-fifth or 75

home position, it is disconnected from ground to open the operating circuit for the operating magnet 3396. Thus, the operation of the rotary switch 3390 is arrested. When the test wiper 3394 is disconnected from ground, the relay R3333 is deenergized and restores. Thus, all of the relay equipment embodied in the local connector switch shown in Fig. 33 is restored to normal and this switch is conditioned for further use.

When the switching relay R3380 restores in response to the restoration of the relay R3320, it disconnects the control conductor C3482 of the called line 60 from ground. When ground potential is removed from this control conductor, the cut-off relay R3440 embodied in the line circuit associated with the line 60 is deenergized and restores. Upon restoring, the relay R3440 opens, at RA3445, the operating circuit for the lockout relay R3430, which latter relay now restores to reprepare, at RA3431, the path for impressing battery potential upon the control conductor C3487 and to reprepare, at RA3432, the path for impressing ground potential upon the distributor start conductor C3433. Following the restoration of the relay R3430, the line circuit illustrated in Fig. 34 and associated with the line 60 is fully released. In the case of a connection routed to a subscriber's line of the multiplex type, the restoration of the switching relay R3380 to remove ground potential from the control conductor of the called line results in the release of the station selecting apparatus associated with the called line in the usual manner.

The manner in which the switching apparatus provided in the exchange C operates to establish a connection between one of the substations associated with the duplex line 60 and another substation line, as, for example, the line 59 extending to the exchange C, on a call originated on the line 60, is substantially the same as described above, the only departure from the described operation pertaining to the mode of operation of the line circuit associated with the calling line 60. Briefly to consider the operation of this line circuit, if the call is initiated at the substation Ts, a circuit is completed for energizing the upper winding of the line relay R3400 in series with the lockout relay R3470 when the receiver at the calling substation is removed from its supporting hook to cause the switch hook arm 3457 to be operated into engagement with its associated contact spring 3456. This circuit may be traced as extending from ground at RC3473 by way of RA3472, the winding of R3470, the transmitter 3459, the receiver 3458, the hook switch arm 3457, the contact spring 3456, the pulsing springs of the calling device 3493, RA3451, C3481, RA3441 and the upper winding of R3400 to battery. Due to the relatively high resistance of the upper winding of the relay R3400, the relay R3470 does not operate over the circuit just traced. The relay R3400, however, operates to complete, at RA3403, an obvious circuit for energizing the respective windings of the relays R3410 and R3420 in parallel. At RA3402, the relay R3400 prepares a holding circuit for itself. At RA3401 and RA3404, the relay R3400 reverses the connections of the line conductors C3481 and C3483 to the link line conductors C3486 and C3488 extending to the bank contacts of the finder switch embodied in the switching selector repeater shown in Figs. 28 and 29. The relay R3410, upon operating, prepares, at RA3411, a circuit, traced hereinafter, for energizing the

operating magnet 3489 of the metering device associated with the substation T_5 . The relay R3420, upon operating, completes, at RA3421, the above-mentioned path for impressing battery potential upon the control conductor C3487, thereby to mark the calling line in the bank contacts of the finder switches respectively embodied in the switching selector repeaters provided in the exchange C. This path extends from battery through the winding of the cut-off relay R3440 and by way of RA3431 and RA3421 to the control conductor C3487. At RA3422 and its associated working contact, the relay R3420, upon operating, completes an obvious path for impressing ground potential upon the control conductor C3482, whereby the calling line 60 is marked as busy in the bank contacts of the connector switches having access to this line. At RA3423, the relay R3420, upon operating, completes a path extending by way of RA3432 for impressing ground potential upon the distributor start conductor C3433. When ground potential is impressed upon the start conductor C3433, the distributor illustrated in Fig. 30 operates to assign to the calling line an idle one of the switching selector repeaters and to initiate the operation of the finder portion of the assigned repeater to seize the calling line, all in the manner explained above with reference to the call initiated at the substation T_4 . Also, when one of the switching selector repeater links is assigned to the use of the calling line, the assigned link is caused to operate to select an idle one of the repeaters associated with a trunk line extending to the exchange B and is conditioned to respond to the impulses of the first digit dialed at the calling substation.

Assuming that the link illustrated in Figs. 28 and 29 is the link assigned to the use of the calling line 60, when the finder switch 2800 operates to seize the line 60, the calling loop circuit is extended to the line terminals of the relay R2820 to complete a holding circuit for this relay and ground potential is impressed upon the control conductor C3487 to complete a circuit for energizing the cut-off relay R3440. The circuit for energizing the cut-off relay R3440 is completed immediately the wipers of the rotary switch 2800 engage the contacts terminating the conductors of the line 60 and before the relay R2810 operates. This circuit may be traced as extending from ground at RA3053 by way of the lower winding of R3040, the lower winding of R3030, RA3023, the test conductor C3056, the upper winding of R2810, the wiper 2802, C3487, RA3421, RA3431 and the winding of R3440 to battery. When this circuit is completed the cut-off relay R3440 fully operates before the switching relay R2810 assumes its fully operated position. The cut-off relay R3440, upon operating, first closes the "X" contacts respectively associated with RA3442 and RA3444. At RA3442, the relay R3440 completes a holding circuit for the relay R3400, this holding circuit extending from ground at RA3402 by way of RA3442 and the upper winding of R3400 to battery. At RA3444, the relay R3440 completes an obvious holding circuit for itself. At RA3441 and RA3446, the relay R3440 disconnects the line terminals of the relay R3400 from the line conductors C3481 and C3483 of the calling line 60. At RA3443, the relay R3440 prepares a further point in the circuit, traced hereinafter, for energizing the operating magnet 3489 of the metering device associated with the substation T_5 . At RA3445, the relay R3440 completes an obvious

5 circuit for energizing the lock-out relay R3430, which latter relay, upon operating, completes, at RA3432, an obvious holding circuit for itself; opens, at RA3431, a point in the operating circuit for R3440; and opens, at RA3432 and its associated resting contact, a point in the previously traced path for impressing ground potential upon the distributor start conductor C3433. The removal of ground potential from this start conductor initiates the release of the distributor shown in Fig. 30 in the manner explained previously. When the switching relay R2810 embodied in the switching selector repeater operates, the lockout relay R3470 provided at the substation T_5 is energized in series with the upper winding of the line relay R2820. The circuit for energizing the relay R3470 may be traced as extending from ground at RC3473 by way of RA3472, the winding of R3470, the transmitter 3459, the receiver 3458, springs 3457, 3458, the pulsing springs of the calling device 3493, RA3451, C3481, RA3401, C3488, the wiper 2801, RA2811 and the upper winding of R2820 to battery. The resistance of the upper winding of the relay R2820 is relatively low as compared with the resistance of either of the two windings of the relay R3400, so that the circuit traversing the winding of the relay R3470 is substantially increased and this relay operates. Upon operating, the relay R3470 first completes, at RA3471 and RA3472, an alternative circuit for maintaining itself energized in series with the two windings of the relay R2820, and thereafter opens, at RA3472 and RC3473, its operating circuit as traced above. The alternative circuit for energizing the relay R3470 is substantially similar to the operating circuit for this relay as traced above, but extends to ground over a path which may be traced as extending by way of RA3472, 40 RA3471, C3483, RA3404, C3486, the wiper 2803, RA2816 and the lower winding of R2820 to ground at RA2821. The current traversing this alternative circuit is sufficient to maintain the relay R3470 operated. Following the operation 45 of the lockout relay R3430, the line circuit associated with the calling line 60 and shown in Fig. 34 is fully operated and no further operation of the apparatus embodied therein occurs until the call is extended to the desired substation and is answered at this substation. The manner in 50 which the call is routed through the switching selector repeater shown in Figs. 28 and 29 and the local connector switch shown in Fig. 33 to the called line 59 is in all respects identical with the operation of this apparatus to extend a connection to the line 60, in the manner set forth previously. When the call is answered at the called substation, the battery reversing relay R3300 embodied in the operated local connector switch is caused to operate to reverse the direction of current flow through the upper winding of the relay R2830, which latter relay now operates to complete, at RA2832, the previously described path for impressing ground potential 55 upon the metering conductor C3489. When ground potential is impressed upon the last-mentioned conductor, the operating magnet 3489 embodied in the metering device associated with the calling device T_5 is energized over a circuit which may be traced as extending by way of the grounded conductor C3489, RA3443, RA3411 and its associated working contact, and the winding of the magnet 3489 to battery. When energized over this circuit, the operating magnet 3489 embodied in the metering device associated with the

calling substation operates to cause the metering device to register the call.

During the release of the connection established as a result of the call initiated at the substation T_5 , and when the calling loop circuit is interrupted at the calling substation T_5 , the lockout relay $R3470$ provided at the substation T_5 is caused to restore, in the manner explained above. During the release of the switching selector repeater shown in Figs. 28 and 29, ground potential is removed from the control conductor $C3487$ with the result that the cut-off relay $R3440$ is deenergized and restores. Upon restoring, this relay opens, at $RA3442$, the holding circuit for the relay $R3400$ and interrupts, at $RA3445$, the operating circuit for the relay $R3430$. The relay $R3400$ now restores to open, at $RA3403$, the operating circuit for the relays $R3410$ and $R3420$. When the last-mentioned relay restores, it opens, at $RA3423$, the holding circuit for the lockout relay $R3430$, which latter relay, upon restoring, reprepares the path for impressing ground potential upon the distributor start conductor $C3433$ and reprepares a point in the above-traced path for impressing marking battery potential upon the control conductor $C3481$. Thus, the line circuit associated with the line 60 and illustrated in Fig. 34 is entirely released.

The mode of operation of the line circuit shown in Fig. 34 when a call is initiated at the substation T_5 is somewhat different from the operation of this circuit as described in the immediately preceding paragraph. More particularly, when the subscriber at the substation T_5 removes his receiver from its hook to initiate the call, a circuit is completed for energizing the lower winding of $R3400$ in series with the winding of the lockout relay $R3450$ provided at the substation T_5 . This circuit may be traced as extending from ground at $RC3453$, by way of $RA3452$, the winding of $R3450$, the transmitter 3479 , the receiver 3478 , the hook switch arm 3477 , the contact spring 3476 , the pulsing springs of the impulsive device 3494 , $RA3471$, $C3483$, $RA3446$ and the lower winding of $R3400$ to battery. Due to the relatively high resistance of the lower winding of $R3400$, the lockout relay $R3450$ does not operate when energized over this circuit. The relay $R3400$, on the other hand, operates to complete the operating circuit for the two relays $R3410$ and $R3420$ and to prepare, at $RA3402$, a circuit for energizing its own upper winding. At $RA3401$ and $RA3404$, the relay $R3400$, upon operating, reverses the connections between the line conductors $C3481$ and $C3483$ and the link line conductors $C3486$ and $C3488$. Thereafter, and when the cut-off relay is energized in the manner explained previously, it operates to complete, at $RA3442$, the previously traced circuit for energizing the upper winding of the relay $R3400$. The last-mentioned relay is differentially wound so that, when both of its windings are energized, it is deenergized and restores. Upon restoring, the relay $R3400$ opens, at $RA3403$, the operating circuit for the relays $R3410$ and $R3420$ and interrupts, at $RA3402$, a point in the circuit, traced above, for energizing its upper winding. At $RA3401$ and $RA3404$, the relay $R3400$ again reverses the connections between the link line conductors $C3486$ and $C3488$ and the line conductors $C3481$ and $C3483$. Upon restoring, the relay $R3410$ opens a point in the operating circuit for the magnet 3489 and prepares the operating circuit for the magnet 3490 of the metering device associated with the substation T_5 . When

5 the relay $R3400$ is caused to restore in response to the partial operation of the cut-off relay $R3440$ in the manner just explained, the lockout relay $R3450$ provided at the substation T_5 is energized in series with the upper winding of the line relay $R2820$ embodied in the operated switching selector repeater. The circuit for energizing the relay $R3450$ may be traced as extending from ground at $RC3453$, by way of $RA3452$, the winding of $R3450$, the transmitter 3479 , the receiver 3478 , the hook switch arm 3477 , the contact spring 3476 , the pulsing springs of the calling device 3494 , $RA3471$, $C3483$, $RA3404$, $C3488$, the wiper 2801 , $RA2811$ and the upper winding of $R2820$ to battery. As pointed out above, the resistance of the upper winding of $R2820$ is relatively low as compared with the resistance of either of the two windings of $R3400$ so that the current traversing the winding of $R3450$ is substantially increased and this relay operates. Upon operating, the relay $R3450$ first completes, at $RA3451$ and $RA3452$, an alternative circuit for maintaining itself energized in series with the two windings of $R2820$, and thereafter opens, at $RA3452$ and $RC3453$, its operating circuit as traced above. The alternative circuit just mentioned is substantially similar to the operating circuit for the relay $R3450$ but terminates at ground over a path which may be traced as extending by way of $RA3452$, $RA3451$, $C3481$, $RA3401$, $C3486$, the wiper 2803 , $RA2816$ and the lower winding of $R2820$ to ground at $RA2821$. The current traversing this alternative circuit is sufficient to maintain the relay $R3450$ operated. The operating circuit for the magnet 3490 is completed in response to the operation of the relay $R2830$, which occurs when the call is answered at the called substation. Thus, the arrangement of the line circuit is such that the apparatus embodied therein discriminates between calls originating at the substation T_5 and calls originating at the substation T_6 , the operation being such that the calls are correctly charged to the substations at which they are initiated. The manner in which the line circuit shown in Fig. 34 restores to normal, during the release of the connection established as a result of the call originating at the substation T_5 , is substantially similar to the release of this circuit is described above with reference to the call originating at the substation T_5 . When, however, the call originates at the substation T_6 , only the two relays $R3440$ and $R3430$ are operated after the connection is fully established. These two relays sequentially restore, in the order named and in the manner explained above, when ground potential is removed from the control conductor $C3487$ during the release of the operating switching selector repeater.

If a calling subscriber initiates a call by removing his receiver from its hook and fails to dial the directory number of the desired party within a reasonable length of time, or a permanent calling condition is otherwise created on one of the subscriber's lines terminating at the finder switches of the switching selector repeaters, the switching selector repeater which is assigned to the use of the line having the calling condition thereon is automatically released and the calling line is locked out of service until the calling condition is removed therefrom. Thus, referring again to the call initiated at the substation T_5 and routed to the switching selector repeater link shown in Figs. 28 and 29, it will be recalled that, when the relay $R2940$ operates in

response to the operation of the hold relay R2825 it completes, at RA2941, a circuit for energizing the heating coil 2858 of the thermal relay 2857. Ordinarily, this circuit is interrupted at RA2911 in response to the operation of the relay R2910 during the dialing of the first digit. If, however, no dialing operation is performed, this circuit is held completed and, after a time interval, the bimetallic element of the thermal relay 2857 operates to close the contacts 2860 and thereby complete a circuit including the resistor 2863 for energizing the heating element 2862 of the thermal relay 2861. After a further time interval, the last-mentioned thermal relay operates to open the contacts 2864, thereby to interrupt the previously traced holding circuit for the relay R2810 and to remove ground potential from the control conductor C3487 of the calling line 60. The switching relay R2810, upon restoring opens the circuit over which the two windings of the line relay R2820 are being held energized in series with the lockout relay R3470, causing both of these relays to restore. When ground potential is removed from the control conductor C3487, the cut-off relay R3440 embodied in the line circuit associated with the calling line 60 is deenergized and restores to open, at RA3442, the holding circuit for the relay R3400 and to recomplete, at RA3441, the original operating circuit for the relay R3400. In this regard, it is pointed out that, if the call originates at the substation T₅ rather than the substation T₆, the relay R3400 is restored at the time the cut-off relay R3440 restores so that the original operating circuit for R3400 is again completed at RA3446. In either case, the relay R3400 is caused to reoperate in response to the restoration of the relay R3440 and, upon reoperating, again completes the operating circuit for the two relays R3410 and R3420. The last-mentioned relay, upon operating, completes, at RA3423, a holding circuit extending by way of RA3432 for the operating slow-to-release line lockout relay R3430. At RA3422, the relay R3420 opens a point in the path by way of which ground potential is extended from the control conductor C3487 to the control conductor C3482 and completes an obvious alternative path for maintaining ground potential upon the last-mentioned control conductor, thereby to hold the line 60 marked as busy in the bank contacts of the connector switches provided in the exchange C. The four relays R3400, R3410, R3420 and R3430 remain in their respective operated positions until such time as the calling condition present on the line 60 is removed from this line. Thus, if the calling condition is the result of a call initiated at one of the substations T₅ and T₆, the release of the line circuit shown in Fig. 34 is initiated when the calling subscriber hangs up to open the circuit over which the relay R3400 is being held energized. When this relay restores, it causes the three remaining operated relays R3410, R3420 and R3430 to restore in an obvious manner, whereby the line circuit is released and the line 60 is marked as idle in the bank contacts of the connector switches to which this line extends. As explained above, the relay R2810 restores following the operation of the thermal relay 2861, it opens, at RA2911 and RA2916, two points in the loop circuit by way of which the line relay R2820 is being held energized. When the last-mentioned relay restores, it initiates the release of the switching

75 selector repeater shown in Figs. 28 and 29 in the exact manner described previously.

SUBSECTION B.—Extension of the connection to the operator's position in the exchange B or to an operator's position in the exchange A.

As pointed out in the preceding subsection, when the switching selector repeater illustrated in Figs. 28 and 29 and located in the exchange C is seized by the distributor shown in Fig. 30 and assigned to the use of the calling line 59, it operates automatically to seize one of the repeaters, as, for example, that shown in Figs. 26 and 27, associated with a trunk line extending to the exchange B. Moreover, the seized repeater responds to the operation of the line relay R2820 embodied in the switching selector repeater by transmitting a seizing pulse of alternating current over the trunk line 37 to the alternating current repeater shown in Figs. 17 and 18. The last-mentioned repeater responds to the seizing pulse of alternating current by initiating the operation of the distributor 26, shown in Fig. 22, to assign one of local finder-connector links provided in the exchange B to the use of the calling line. If it be assumed, for example, that the repeater illustrated in Figs. 26 and 27, the trunk line 37, the repeater shown in Figs. 17 and 18, and the local finder-connector link of Figs. 19 and 20 are seized in response to the operation of the switching selector repeater shown in Figs. 28 and 29 resulting from the call originating at the substation T₄, this switching equipment is conditioned to respond to the impulses of the first digit dialed at the calling substation before the dialing operation is started and in the manner previously explained. If the connection is to be routed to an operator, the calling subscriber dials the two line selecting digits required to cause the seized local connector switch provided in the exchange B to forward the connection to the operator's position in the exchange B or to an operator's position in the exchange A, depending upon the position occupied by the transfer switch 800. During the impulses of each of these two digits, the relay R2820 alternately restores and reoperates to open and close the contacts associated with RA2821, thereby to repeat the impulses by way of the trunk line 63 to the repeater shown in Figs. 26 and 27. The minor switch 2900 responds to the operation of the line relay R2820 during the impulses of the first digit by operating its wiper 2902 to the off-normal position which corresponds to the number of impulses making up the first digit. When this wiper is stepped to its first off-normal position, the off-normal springs 2905 are closed to complete the operating circuit for the relay R2910, which relay, upon operating, opens, at RA2911, a point in the circuit for energizing the heating coil 2858 of the thermal relay 2857 and interrupts, at RA2913, a point in the original circuit for energizing the relay R2850 in parallel with the minor switch operating magnet 2903. At RA2914, the relay R2910 opens a point in the previously traced path for impressing ground potential upon the guard conductor C3055 corresponding to the switching selector repeater shown in Figs. 28 and 29. At RA2915, the relay R2910 prepares a point in the circuit, traced previously, for energizing the release magnet 2904. As explained above, during the interdigit pause between the first and second series of impulses dialed at the calling substation, the two relays R2840 and R2850 restore. The last-men-

tioned relay, upon restoring, opens, at RA2855, a point in the alternative circuit for energizing the operating magnet 2903, whereby this operating magnet is prevented from being energized in accordance with the impulses making up the second digit dialed at the calling substation. On a toll call of the character under consideration, the first digit dialed at the calling substation is, of course, different from the first or preliminary digit dialed when the calling subscriber is making a local call. Specifically, the bank wiring arrangement of the local connector switches located in the exchange B is such that a first series of ten impulses must be transmitted thereto in order to cause a selected one thereof to operate and extend the connection to an operator's position in either the exchange B or the exchange A. Hence, on the call here being considered, the wiper 2902 of the minor switch 2900 is left standing in its tenth off-normal position at the conclusion of the first digit, in which position the wiper is open-circuited and does not provide a circuit for causing the operation of any of the relays embodied in the switching selector repeater shown in Figs. 28 and 29. Thus, when a toll digit of ten impulses is dialed into the switching selector repeater, this unit does not operate to seize one of the local connector switches provided in the exchange C. During the impulses of the second digit, the only relay operations which occur in the switching selector repeater are the alternate restoration and operation of the line relay R2820, and the operation of the slow-acting relay R2840 at the beginning of the first impulse of the second series, followed by its restoration shortly following the end of the second series of impulses.

Before describing the operation of the repeater shown in Figs. 26 and 27 to repeat the impulses which are transmitted thereto from the switching selector repeater of Figs. 28 and 29, and in order to complete the description of the operation of the last-mentioned switching unit, it is pointed out that, in the event this switching selector repeater is seized at a time when all of the trunk lines extending from the exchange C to the exchange B are busy, dial tone is returned from the switching selector repeater to the calling subscriber to indicate that the dialing operation may be started, and the busy trunks are guarded against seizure by the rotary switch 2980. More particularly, when all of the trunk lines extending between the exchanges B and C are busy, all of the contacts included in the level associated with the wiper 2982 with the exception of that terminating the conductor C2991 are grounded. The reason why the indicated conductor C2991 is not grounded when an all-trunks-busy condition exists is that all of the relays corresponding to and including the hold relay R2780 and individually embodied in the respective repeaters associated with the interoffice trunk lines are operated and, hence, all of the multiple paths for impressing ground potential upon the conductor C2991 are open. During the trunk hunting operation of the rotary switch 2980, which occurs in response to the partial operation of the relay R2960 in the manner explained in the preceding subsection, the wipers of the switch 2980 are driven over their respective associated contacts until they are moved into engagement with their respective associated second contacts, at which time the wiper 2982 is connected to the open-circuited conductor C2991. When this occurs, the circuit for energizing the operating magnet 2985 of the

switch 2980 is interrupted and the path short-circuiting the upper winding of the relay R2960 is opened, permitting this relay to complete its operation in the manner explained previously. With the wiper 2984 standing in engagement with its associated second contact and when the relay R2960 fully operates, a path is completed for effectively connecting the high potential side of the dial tone current source provided in the exchange C to the positive side of the line extending to the calling substation. This path may be traced as extending by way of the condenser 2925, RA2916, the wiper 2984, RA2965 and RA2952 to the positive line conductor C2874 of the link line embodied in the switching selector repeater shown in Figs. 28 and 29. The completion of this path results in the transmission of the usual dial tone signal to the calling subscriber. Upon receiving dial tone, the calling subscriber may dial the directory number of the desired party. During the impulses of the first digit dialed at the calling substation, the minor switch 2900 responds, in the manner explained above, by moving its wiper 2902 into engagement with the contact corresponding to the number of impulses making up the first digit. As explained in the preceding subsection, if a local substation is being called, the rotary switch 2980 is caused to operate during the interdigit pause between the first and second digits to select an idle one of the local connector switches provided in the exchange C. Also, during the first series of impulses dialed at the calling substation, the relay R2910 is caused to operate to open, at RA2916, the above-traced path by way of which dial tone current is transmitted to the calling substation, and to prepare a path for transmitting a busy tone signal to the calling subscriber. This path may be traced as extending from the ungrounded terminal of the busy tone current source by way of the condenser 2966, RA2916, and its associated working contact, the wiper 2984, RA2965 and RA2952 to the positive link line conductor C2874. As explained above, if the rotary switch 2980 is caused to operate during the interdigit pause between the first and second digits to select an idle one of the local connector switches provided in the exchange C, the wiper 2984 is moved from engagement with its associated second contact so that the above-traced path is not completed and busy tone is not returned to the calling subscriber. On the other hand, if the call initiated at the calling substation is a toll call and intended for the operator's position in the exchange B or an operator's position in the exchange A, the rotary switch 2980 does not operate during the interdigit pause between the first and second digits. Accordingly, the above-traced path for projecting busy tone current over the calling loop circuit is not interrupted and the usual busy signal is reproduced by the receiver provided at the calling substation, thus indicating to the calling subscriber that the desired connection can not be obtained. The manner in which the switching selector repeater shown in Figs. 28 and 29 is released following the receipt of the busy signal occasioned by the all-trunks-busy condition just described is in all respects similar to the release of this switching unit as described in the preceding subsection.

The arrangement of the relay equipment embodied in the switching selector repeater shown in Figs. 28 and 29 is such that, if a calling subscriber inadvertently fails to dial a first digit indicative of a toll call or, alternatively, indicative of a local call, a busy tone signal is returned to

the calling subscriber, the operated switch train extending to the seized local finder-connector link provided in the exchange B is released, and further digits dialed at the calling substation are without effect. To this end, the relay R2950 is provided and all of the contacts embodied in the contact set 2901 of the minor switch 2900 with the exception of the fourth and tenth contacts are multiplied together and connected in an operating circuit for the relay R2950. With this arrangement, if a first digit comprising any number of impulses other than four impulses or ten impulses is dialed at the calling substation, the wiper 2902 of the minor switch 2900 is left standing in engagement with one of the indicated multiplied contacts at the end of the first digit. During the interdigit pause following the first digit and when the relay R2850 is caused to restore in the manner explained previously, a circuit is completed for energizing the relay R2950, which circuit may be traced as extending from ground at RA2827 by way of RA2854, C2868, the wiper 2902, one of the multiplied contacts of the set 2901, and the winding of R2950 to battery. When energized over this circuit, the relay R2950 operates to complete, at RA2951 and its associated working contact, an obvious holding circuit for itself. At RA2952, the relay R2950 completes an obvious path for effectively connecting the busy tone current source to the positive link line conductor C2874, whereby the usual busy tone signal is returned to the calling subscriber. At RA2951 and its associated resting contact, the relay R2950 opens a point in the respective holding circuits for the relays R2940 and R2960, causing both of these relays to restore. The relay R2960, upon restoring, opens, at RA2961 and RA2965, the loop circuit extending to the repeater seized by the rotary switch 2980 during the preliminary operation of the switching selector repeater, thereby to initiate the release of this repeater and the operated switch train in the exchange B, all in the manner explained subsequently. The relay R2940, upon restoring, opens, at RA2945, the operating circuit for the relay R2930. Following the operation of the relay R2950, and the resulting restoration of the relays R2940 and R2960, no further relay operations occur in the switching selector repeater until the connection is cleared out at the calling substation.

As indicated above, the repeater illustrated in Figs. 26 and 27, when seized by the switching selector repeater shown in Figs. 28 and 29 in response to the call initiated at the substation T₄, functions to convert the impulses dialed at the calling substation into alternating current impulses which are transmitted by way of the trunk line 37 to the alternating current repeater located at the distant end of this trunk line and illustrated in Figs. 17 and 18. Thus, each time the line relay R2820 restores to open, at RA2821, the loop circuit extending to the repeater shown in Figs. 26 and 27, the line relay R2775 restores to complete operating circuits for the relays R2630 and R2645, it being pointed out that, following seizure of this repeater, only the three relays R2730, R2775 and R2780 are operated. The operating circuit for the relay R2645 may be traced as extending from ground at RA2777 by way of RA2731, C2682 and the winding of R2645 to battery, while the operating circuit for the relay R2630 extends from ground by way of RA2776, RA2735, C2680 and the winding of R2630 to battery. The relay R2630, upon operating, connects the line conductors C1885 and C1886 of the trunk

line 37 to the opposite terminals of the alternating current source provided in the exchange C in the manner explained previously. The relay R2645 operates at the beginning of the first impulse and, due to its slow-to-release characteristic, remains operated throughout each series of impulses. This relay, at its two armatures RA2646 and RA2647, disconnects the line terminals of the repeating transformer windings 2616 and 2617 from the contact springs controlled by the relay R2630 to prevent alternating current from being returned over the calling loop circuit to the calling substation. Obviously, during the close circuit period of each impulse, the relay R2775 is caused to reoperate to open the respective operating circuits for R2630 and R2645 as traced above. Thus, the relay R2630 follows the impulses and, by connecting the line conductors of the trunk line 37 to the alternating current source provided in the exchange C operates to transmit corresponding impulses of alternating current over the trunk line 37 to the distant repeater shown in Figs. 17 and 18. The relay R2780, due to its slow-to-release characteristic, remains operated during impulsive. At the end of each digit, the relay R2775 remains operated to hold interrupted the above-traced operating circuits for the two relays R2630 and R2645. Accordingly, the two last-mentioned relays restore to reconnect the conductors of the trunk line 37 to the line terminals of the repeating transformer windings 2616 and 2617.

Each time an alternating current pulse is transmitted by way of the trunk line 37 to the repeater shown in Figs. 17 and 18, the alternating current relay R1815 is energized and operates, it being pointed out in the foregoing description that, at the time the first series of impulses is transmitted over the trunk line 37 to the repeater of Figs. 17 and 18, the relays R1750, R1830 and R1865 are operated and the three relays R1800, R1805 and R1810 are operating in a cyclic manner repeatedly to energize the operating magnet 1772 of the minor switch 1770. Upon operating at the beginning of the first impulse of the first series of impulses transmitted by way of the trunk line 37, the relay R1815 completes, at RA1817 and its associated working contact, a circuit for energizing the winding of the slow-acting relay R1760 and the lower winding of R1870 in parallel. This circuit may be traced as extending from ground at RA1817 by way of C1790, RA1737, RA1756 and C1789 to RA1864, where it divides, one branch extending through the lower winding of R1870 to battery and the other branch extending by way of C1788 and the winding of R1760 to battery. Upon operating, the relay R1760 completes, at RA1762, a path extending by way of C1782 for short-circuiting the winding 1874 of the repeating transformer R1873 and completes, at RA1763, a path including the conductor C1786 for shunting the series circuit comprising the transformer winding 1875, the resistor 1767 and the lower winding of the relay R1765. Thus, the two windings 1874 and 1875 of the repeating transformer, the resistor 1767 and the lower winding of R1765 are removed from the loop circuit by way of which the impulses are transmitted to the line relay R2020 embodied in the operated local finder-connector link shown in Figs. 19 and 20.

The relay R1870 also operates, when its lower winding is energized in parallel with the relay R1760 over the circuit traced above. Upon operating, the relay R1870 prepares, at RA1873, a

circuit for energizing its upper winding and completes, at RA1872, a path for short-circuiting the lower winding of R1860, which path may be traced as extending from ground at RA1817 by way of C1790, RA1737, RA1756, C1789, RA1864, the lower winding of R1860, RA1872 and C1794 back to ground at RA1758. At RA1871, the relay R1870 interrupts the operating circuit for the slow-to-release relay R1865 and completes a circuit for energizing the relay R1850, this latter circuit extending from ground at RA1758 by way of C1794, RA1871, RA1866 and the winding of R1850 to battery. The relay R1850, upon operating, prepares, at RA1853, an alternative holding circuit for R1865. At RA1852, the relay R1850 completes an obvious holding circuit for itself. At RA1854, the relay R1850, upon operating, opens a point in the previously traced operating circuit for the relay R1830 so that, during the period of the next operating cycle of the three relays R1800, R1805 and R1810, when the first two thereof restore to open the holding circuit for R1830, the last-mentioned relay restores to arrest the cyclic operation of the three enumerated relays and to complete, at RA1831 and its associated resting contact, the prepared circuit for energizing the release magnet 1773 of the minor switch 1770. This circuit may be traced as extending from ground at RA1831 by way of C1780, the off-normal springs 1774 and the winding of the magnet 1773 to battery. When energized over this circuit, the magnet 1773 operates to return the switch wiper 1771 to normal in the usual manner, at which time the off-normal springs 1774 are opened to interrupt the circuit for energizing the release magnet 1773.

When the first pulse of alternating current transmitted by way of the trunk line 37 is terminated, the relay R1815 restores to open, at RA1817 and its associated working contact, a point in the previously traced path short-circuiting the lower winding of the relay R1860, permitting this winding to be energized in series with the lower winding of the relay R1870. Upon restoring, the relay R1815 also completes, at RA1817 and its associated resting contact, an alternative holding circuit for the operated slow-to-release relay R1865, this circuit extending from ground at RA1817 by way of RA1853, RA1867 and the winding of R1865 to battery. The relay R1860 operates, when its lower winding is energized in series with the lower winding of the relay R1870 and, upon operating, completes, at RA1862, an obvious path for short-circuiting its upper winding, thereby to render itself slow to release. At RA1864, the relay R1860 opens a further point in the previously traced circuit for energizing the lower winding of the relay R1870 in parallel with the winding of the relay R1760. At RA1861, the relay R1860 completes the above-mentioned circuit extending by way of RA1873 for energizing the upper winding of the relay R1870. At RA1863, the relay R1860 opens a point in the loop circuit extending to the local finder-connector link shown in Figs. 19 and 20, thereby to repeat the impulse to the line relay R2035 embodied in the local finder-connector link. When its upper winding is energized in response to the operation of the relay R1860, the relay R1870, which is differentially wound, restores to open, at RA1872, a point in the energizing circuit for the lower winding of the relay R1860. After a time interval determined by its slow-to-release characteristic, the relay R1860 restores to re-

complete, at RA1863, the loop circuit extending to the operated local finder-connector link and to open, at RA1861, a point in the above-traced circuit for energizing the upper winding of the relay R1870. At RA1864, the relay R1860 reprepares the above-traced circuit for energizing the lower winding of the relay R1870 in parallel with the winding of the relay R1760, whereby the two last-mentioned relays are again energized in response to the operation of the relay R1815 at the beginning of the next alternating current pulse transmitted by way of the trunk line 37. During each succeeding impulse dialed at the calling substation, the two relays R1860 and R1870 interact, in the exact manner just explained, and the relay R1860 functions to repeat the impulses to the operated local finder-connector link provided in the exchange B. During this series of impulses, the two relays R1760 and R1865, each of which is of the slow-to-release type, remain operated.

During the interdigit pause between each pair of digits dialed at the calling substation, the relay R1760 restores, it being understood that the relay R1860 also restores shortly following the end of the last impulse of each digit. The manner in which the slow-acting relay R1760 operates at the beginning of the first impulse of each series of impulses and the manner in which the two relays R1870 and R1860 interact to repeat the impulses of the second series to the operated local finder-connector link are in all respects similar to the operations of these relays as described above with reference to the impulses of the first digit. It will be apparent that the two relays R1860 and R1870 comprise an impulse correcting network and operate in a manner substantially similar to that described previously with reference to the corresponding relays R1160 and R1170 embodied in the repeater of Figs. 10 and 11 to render the ratio of the opened to closed periods of each impulse transmitted to the local finder-connector link substantially independent of the duration of the corresponding alternating current pulse transmitted by way of the trunk line 37.

During impulsive, the line relay R2035 embodied in the local finder-connector link shown in Figs. 19 and 20 is energized over a circuit which may be traced as extending from ground by way of the lower winding of R2035, RA2046, RA2054, the wiper 2073, C2326, RA1759, C1796, C1786, RA1763, RA1755, C1787, RA1863, C1782, RA1762, C1775, RA1751, C2325, the wiper 2071, RA2051, RA2041, and the upper winding of R2035 to battery. Since the armature RA1863 of the pulsing relay R1860 is included in this circuit, the circuit is obviously interrupted during each impulse in response to the operation of R1860 as explained above. Thus, the line relay R2035 is caused to follow the impulses dialed at the calling substation for the purpose of controlling the connector portion of the operated finder-connector link to select a trunk line extending to the operator's position in the exchange B. The manner in which the connector portion of the finder-connector link operates to forward the connection to the operator's position is exactly the same as set forth in Section 7—Subsection A. Also, if the operator in the exchange B is not on duty at the time the call under consideration is initiated, the connection is routed to an operator's position in the exchange A in the exact manner described in Section 7—Subsection B. Assuming that the connection is routed to the operator's position

in the exchange B, it may further be extended to a substation line terminating at any one of the exchanges A, D, E and F in the manner described in the appropriate subsections of Section 7 of this specification. If the connection as extended to the operator's position in the exchange B is to be extended to a substation line terminating at the exchange B, the desired connection may be completed under the supervision of the operator in the exchange B, as explained in Section 9—Subsection A. Alternatively, if the operator in the exchange B is off duty, such that the connection is routed to an operator's position in the exchange A, in the manner explained in Section 7—Subsection B, it may further be extended from this operator's position to a desired substation line terminating at any one of the exchanges A, B, D, E and F, in the manner set forth in the appropriate subsections of section 9.

The release of the operated switch train utilized in forwarding the connection from an operator's position to the desired substation is entirely under the control of the operator in the exchange B or an operator in the exchange A as the case may be. Also, if the connection is routed by way of the local finder-connector link of Figs. 19 and 20, the repeater illustrated in Figs. 10 and 11 and the trunk lines 28 and 12 to the operator's position equipment shown in Fig. 4, the release of the repeater and the trunk circuit apparatus of Fig. 4 is initiated when the operator in the exchange A clears out the connection, and is accomplished in the manner explained in Section 7—Subsection B. On the other hand, the release of the switching equipment by way of which the connection is routed through a local finder-connector link in the exchange B is entirely under the control of the calling subscriber at the substation T₄. Thus, when the calling subscriber at the substation T₄ hangs up, the operated switching selector repeater shown in Figs. 28 and 29 is caused to release in the manner explained in the preceding subsection of this section. During the release of the switching selector repeater, the loop circuit extending by way of the trunk line 63 to the repeater shown in Figs. 26 and 27 is interrupted, thereby to initiate the release of this repeater. In this regard it will be recalled from the preceding subsection that, if the switching selector repeater of Figs. 28 and 29 is used to complete a local connection between two substation lines terminating at the exchange C, the loop circuit extending to the repeater shown in Figs. 26 and 27 is opened shortly after the first digit is dialed at the calling substation. When the loop circuit extending by way of the trunk line 63 to the repeater shown in Figs. 26 and 27 is opened, the line relay R2775 is deenergized and restores to open, at RA2776, the operating circuit for the slow-acting hold relay R2780. The last-mentioned relay, upon restoring, completes, at RA2782, a circuit extending by way of RA2734 and C2679 for energizing the upper winding of the relay R2640, causing the last-mentioned relay to operate and initiate the cyclic operation of the three relays R2655, R2660 and R2670 in the manner explained previously. The line relay R2775, upon restoring, also completes the previously traced operating circuits for the two relays R2630 and R2645. The relay R2630, upon operating, connects the conductors of the trunk line 37 to the alternating current source provided in the exchange C, thereby to transmit

a relatively long pulse of alternating current over the trunk line 37 to the repeater terminating the distant end of this line. As explained in the preceding section of the specification, with the relay R2640 operated, the circuit for energizing the operating magnet 2787 of the minor switch 2785 is momentarily completed during each cycle of operation of the three relays R2655, R2660 and R2670. As a result, the wiper 2786 of the minor switch 2785 is stepped over its associated contacts until it is operated to its fifth off-normal position, at which time a path is completed for short-circuiting the winding of the operated relay R2730, this path extending from ground at RA2733 by way of the switch wiper 2786, the winding of R2730 and RA2738' back to ground at RA2717. The relay R2730 now restores to open, at RA2738', a point in its holding circuit and to open, at RA2735, RA2734 and RA2731, respectively, points in the respective operating circuits for the three operated relays R2630, R2640 and R2645, causing the relays R2630 and R2645 to restore. At RA2732, the relay R2730, upon restoring, disconnects the control conductor C2895 of the trunk line 63 from ground, thereby to mark the repeater shown in Figs. 26 and 27 as idle in the bank contacts of the switching selector repeaters and the incoming connector switches having access thereto. Following the interruption of the operating circuit for the relay R2640 and during the period of the next operating cycle of the three relays R2655, R2660 and R2670 when the last two thereof are restored, the holding circuit for R2640 is interrupted and this relay restores. Upon restoring, the relay R2640 arrests the cyclic operation of the three relays R2655, R2660 and R2670, in the manner explained previously, and completes the previously traced circuit for energizing the release magnet 2188 embodied in the minor switch 2785. The wiper 2786 of the minor switch is thus returned to normal, at which time the off-normal springs 2789 are opened to interrupt the operating circuit for the release magnet. When the relay R2630 restores in the manner explained above, it disconnects the line conductors of the trunk line 37 from the alternating current source provided in the exchange C, thereby to terminate the alternating current release pulse transmitted by way of the trunk line 27 to the distant repeater located in the exchange B and illustrated in Figs. 17 and 18. Following the release of the minor switch 2785, all of the control equipment embodied in the repeater shown in Figs. 26 and 27 is returned to normal and this repeater is conditioned for further use. The alternating current relay R1815 embodied in the repeater shown in Figs. 17 and 18 responds to the relatively long pulse of alternating current transmitted thereto over the trunk line 37 by operating to open, at RA1817 and its associated resting contact, the previously traced holding circuit for the slow-to-release relay R1865 and to complete, at RA1817 and its associated working contact, the previously traced circuit for energizing the lower winding of the relay R1870 in parallel with the winding of the relay R1760. Upon operating, the relay R1870 short-circuits the lower winding of the relay R1860 and prepares the circuit for energizing its own upper winding, in the manner previously described. Since the alternating current release pulse endures for a relatively long time interval, the relay R1815 is held operated for a sufficient length of time to permit the slow-to-release re-

lay R1865 to restore. Upon restoring, the last-mentioned relay completes, at RA1868, a circuit extending from ground at RA1855 for energizing the lower winding of the relay R1830, causing the last-mentioned relay to reoperate and initiate the cyclic operation of the three relays R1800, R1805 and R1810 in the manner explained previously. Thus, the operation of the minor switch 1770 is initiated and continues until the wiper 1771 is operated to its third off-normal position, at which time a circuit is completed for energizing the relay R1745, this circuit extending from ground at RA1817 by way of C1790, RA1737', RA1756, C1789, RA1864, C1788, the wiper 1771 and the winding of R1745 to battery. When energized over this circuit, the slow-to-release relay R1745 operates to interrupt, at RA1741 and RC1748, the original holding circuit for the relay R1750 and completes, at RA1746 and RA1747, an alternative holding circuit for itself and the relay R1750. This alternative holding circuit may be traced as extending from ground at RA1817 by way of C1790, RA1737' and RA1756 to RA1749, where it divides, one branch extending through the winding of R1745 to battery, and the other branch extending by way of RA1746, RA1747 and the two series connected windings of R1750 to battery. The relays R1745 and R1750 are held energized over this alternative holding circuit until the alternating current release pulse is terminated to cause the restoration of the relay R1815. When the relay R1815 restores the above-traced alternative holding circuit for R1750 and the relay R1745 is interrupted at RA1817. Due to the slow-to-release characteristic of the relay R1745, the relay R1750 falls back before the relay R1745 restores. Upon restoring, the relay R1815 also opens, at RA1817, the above-traced operating circuit for the relay R1760 and a point in the path short-circuiting the lower winding of the relay R1870. The lower winding of the relay R1870 is momentarily energized in series with the lower winding of the relay R1860 over the circuit traced previously, but shortly thereafter the relay R1750 restores to open this circuit at RA1758. Thus, the three relays R1760, R1860 and R1870 are caused to restore. Upon restoring, the relay R1750 opens, at RA1754, a point in its original holding circuit. At RA1751 and RA1759, the relay R1750 opens two points in the previously traced loop circuit extending to the operated local finder-connector link shown in Figs. 19 and 20. Shortly following the restoration of the relay R1750, the slow-to-release relay R1745 restores to reprepare, at RA1741 and RC1748, the original holding circuit for the relay R1750. At RA1757, the relay R1750, upon restoring, opens the circuit for energizing the upper winding of R1765 and a point in the original operating circuit for the relay R1830. At RA1752, the relay R1750 opens the previously traced path for applying ground potential to the control conductor C1319 of the trunk line 32, thereby to mark this line as idle in the bank contacts of the numerical switches having access thereto. At RA1758, the relay R1750 opens the holding circuit for the relay R1850, causing the last-mentioned relay to restore. When the relay R1850 restores, it opens, at RA1855, a point in the above-traced alternative operating circuit for the relay R1830, so that, during the period of the next operating cycle of the three relays R1800, R1805 and R1810 when the first two thereof are restored to open the holding circuit for the re-

lay R1830, the relay R1830 restores. Upon restoring, the relay R1830 opens points in the respective operating circuits for the minor switch operating magnet 1772 and the two relays R1800 and R1805, thereby to arrest the cyclic operation of the three relays R1800, R1805 and R1810 and the operation of the minor switch 1770. Upon restoring, the relay R1830 also completes the previously traced circuit for energizing the release magnet 1773, whereby the wiper 1771 of the switch 1770 is caused to be returned to its home position in the usual manner. When the switch wiper 1771 is restored to its home position, the off-normal springs 1774 are opened to interrupt the operating circuit for the release magnet 1773. Following the release of the minor switch 1770, the control apparatus embodied in the repeater shown in Figs. 17 and 18 is restored to normal and this repeater is conditioned for further use.

When the loop circuit extending through the local finder-connector link of Figs. 19 and 20 to the operator's position in the exchange B or to one of the repeaters associated with a trunk line extending to the operator's position in the exchange A is interrupted, the supervisory lamp, utilized to indicate the condition of the connection and located at either of the two operators' positions, is energized in the manner explained previously. The illumination of this lamp indicates to the operator that the connection is ready for release. The manner in which the local finder-connector link shown in Figs. 19 and 20 is released when the connection is routed to the operator's position 14 located in the exchange B is explained in Section 7—Subsection B, whereas the manner in which this link is released when the connection is routed to the operator's position 10 located in the exchange A is explained in Section 7—Subsection C.

SECTION 9.—CONNECTION ROUTED TO AN OPERATOR'S POSITION IN THE EXCHANGE A AND EXTENDED THROUGH THE EXCHANGE B TO THE DESIRED SUBSCRIBER'S SUBSTATION

SUBSECTION A.—Extension of the connection to the operator's position in the exchange B

If a call, originating on a line terminating at the exchange A or on a line terminating at the exchange D and intended for a subscriber having a substation associated with a line terminating at one of the exchanges B, C, E and F, is routed to the operator's position in the exchange A, the answering operator may utilize one of the trunk lines in the group including the line 12 in forwarding the connection to the desired line. Assuming that the call is routed to the operator's position 10 and that the trunk line 12 is to be utilized in forwarding the connection to the desired substation, the manner in which the equipment shown in Fig. 4 operates is dependent upon the position of the transfer switches 483 and 800. More particularly, if the call is initiated at a time when the operator in the exchange B is on duty, each of the transfer switches 483 and 800 occupies its off-normal position, whereas, if the call originates at a time when the operator in the exchange B is off duty, each of the transfer switches occupies its normal or restored position. To initiate the call when the operator in the exchange B is on duty, the operator in the exchange A inserts the call and answer plug terminating her telephone cord circuit in the jack 482 and operates the ringing key provided in the

cord circuit, thereby to cause ringing current to be projected over the trunk line 12. More particularly, when the calling operator operates her ringing key, ringing current is caused to traverse a circuit comprising the tip and ring contacts of the jack 482, the switch springs 485 and the winding 480 of the repeating transformer 475. The resulting induced voltages developed in the transformer windings 476 and 477 cause the alternating current relay R630 to be energized over a closed circuit which may be traced as extending from the upper terminal of the winding 476 by way of RA406, C413, the switch springs 801 and 802, C834, RA646, the winding 604, the winding of R630, the condenser 631', the winding 605, RA647, C835, the switch springs 805 and 804, C414, RA408, the winding 477, the condenser 478, the winding of R470, and the winding 476. The relay R470 operates when energized over the circuit just traced and completes, at RA472, an obvious circuit for energizing the lower winding of the relay R450 but the resulting partial operation of the last-mentioned relay is without effect. The relay R630 also operates when energized over the above-traced circuit and, upon operating, interrupts, at RA631, the normally closed holding circuit for the slow-to-release relay R635. The relay R635 restores after an interval to open, at RA638, a further point in its holding circuit and to complete, at RA639, a circuit for energizing the line signal lamp 649, this latter circuit extending from ground at RA639 by way of the switch springs 615 and 614, the filament of the lamp 649, C544 and the winding of R520 to battery. At RA637, the relay R635 prepares a point in its operating circuit as traced hereinafter. When the lamp 649 is energized over the circuit just traced, it is illuminated to provide a visual signal that a calling condition exists upon the trunk line 12. Also, if the switch 513 occupies its off-normal position when the relay R520 is energized in series with the signal lamp 649, the operation of the buzzer 525 is initiated. Thus, the visual signal is supplemented by an audible signal to attract the attention of the operator.

The operator in the exchange B answers the call by operating the call and answer switch 619 to its off-normal position to close the springs 620 and 628 and connect the operator's telephone set across the line terminals of the repeating transformer windings 601 and 602. At the springs 625, the previously-traced circuit is completed for energizing the transmitter 500, thereby to condition this transmitter for use in communicating over the established connection. At the springs 626, an obvious circuit is completed for energizing the line busy lamp 648 and, at the springs 624, an obvious circuit is completed for again energizing the slow-to-release relay R635. When the relay R635 reoperates, it completes, at RA638, its holding circuit and opens, at RA639, the above-traced circuit for energizing the line signal lamp 649 in series with the relay R520. Thus, the lamp 649 is extinguished and operation of the buzzer 525 is arrested. At RA637, the relay R635 opens a point in its alternative operating circuit as traced hereinafter. Following the operation of the switch 619 to its off-normal position, a talking circuit, including the trunk line 12, is fully completed between the operator's position 10 in the exchange A and the operator's position in the exchange B, whereby the calling operator in the exchange A may transmit to the operator in the exchange B the name or telephone number of the party desired.

5 by the calling subscriber. The manner in which the connection may be extended from the operator's position in the exchange B to a subscriber's line terminating at any one of the exchanges C, D, E and F is explained in the appropriate subsection of Section 7.

10 If a call is to be forwarded to a subscriber's line terminating at the exchange B, the answering operator located in the exchange B may route the connection to the desired substation line by operating the switch 764 to its off-normal position to seize the incoming connector switch shown in Figs. 12 and 13, in the manner explained in Section 7, Subsection D, and thereafter dialing the digits of the directory number designating the desired substation. The manner in which the incoming connector switch of Figs. 12 and 13 operates to select a subscriber's line is somewhat different from the trunk selecting operation of the switch as described in the indicated preceding portion of the specification. Thus, the arrangement is such that, if the subscriber's line to be selected is of the single party or duplex type, the relay R1304 is energized and operates during the line selecting operation of the connector switch, whereas, if the line to be selected is of the multiplex type, the relay R1304 does not operate. More particularly, the multiplex lines extending to the exchange B are terminated in the lowermost levels of the bank contact field embodied in the Strowger switching mechanism 1370. For example, if twenty-five multiplex lines extend to the exchange B, the first two contact levels and half of the third level of the bank contact field are utilized in terminating these lines. The last half of the third level and the succeeding levels may be used to terminate subscribers' lines of the single party or duplex type. For the purpose of controlling the relay R1304, the off-normal springs 1398 are provided, which springs are arranged to operate during the vertical movement of the wipers 1371 to 1374, inclusive, only after the wipers are operated to a position opposite the level of contacts next succeeding the last level having lines of the multiplex type terminated thereat. Also, the switching mechanism 1370 is provided with an extra control bank contact field having contacts arranged to be engaged by the wiper 1374. In the assumed arrangement, wherein the third level of contacts terminates both multiplex and single party or duplex lines, the multiplex lines are terminated at the first five sets of contacts in the level and the duplex or single party lines are terminated at the last five sets of contacts in the level. The sixth extra control contact of this third level, namely, that corresponding to the first single party or duplex line terminated at the level is connected to ground through a resistance of approximately one thousand ohms so that, when the wiper 1374 encounters this contact during rotary movement thereof, the relay R1304 is caused to operate.

15 Continuing now with the operation of the incoming connector switch, if it be assumed, for example, that the call is to be extended to the subscriber's line 33, the wipers 1371 to 1374, inclusive, of the rotary switch 1370 are operated into engagement with the contacts terminating the conductors of this line in response to the dialing of the appropriate line selecting digits at the operator's position in the exchange B. During the rotary or vertical movement of the switch wipers, a circuit is completed for energizing the relay R1304. If the line 33 terminates at a con-

tact level including only lines of the single party or duplex type, the circuit for energizing the relay R1304 is completed in response to closure of the off-normal springs 1398, this circuit extending from ground at RA1242 by way of C1271, the off-normal springs 1398 and the winding of R1304 to battery. On the other hand, if the line 33 terminates at a contact level of the switching mechanism 1370 also terminating lines of the multiplex type, the circuit for energizing the relay R1304 is completed during rotary movement of the switch wipers and extends by way of the grounded wiper 1374, RA1364, RA1351, RA1306 and the winding of R1304 to battery. When energized over either of these circuits, the relay R1304 first operates to close the "X" contacts associated with RA1307, thereby to complete an obvious holding circuit for itself. At RA1306, the relay R1304, upon fully operating, opens a point in one of its two operating circuits as traced above. At RA1305 and RA1309, the relay R1304 prepares two points in the circuit, traced hereinafter, for energizing the signal device provided at the called substation. At RA1308, the relay R1304 opens a point in one path for short-circuiting the lower winding of the relay R1340.

From the foregoing description, it will be recalled that, at the end of the second digit, the three relays R1335, R1340 and R1350 are operated so that a test circuit is prepared for energizing the busy test relay R1320. Shortly following the end of the digit, the three enumerated relays R1335, R1340 and R1350 are caused sequentially to restore in the order named and in the manner previously explained. Assuming that the called line 33 is idle at the time it is selected, a circuit is completed, in response to the restoration of the relay R1350, for energizing the lower winding of the line switching relay R1360. This circuit may be traced as extending from ground at RA1241 by way of C1265, RA1322, the off-normal springs 1397, the lower winding of R1360, RA1341, RA1352 and the test wiper 1373 to battery as impressed upon the control conductor C1382 through the winding of the cut-off relay R2260 embodied in the line circuit associated with the called line 33. When its lower winding is energized over this circuit, the relay R1360 partially operates to complete, at the "X" contacts associated with RA1367, a circuit extending from ground at RA1242 and by way of C1271 for energizing its upper winding. The relay R1360 now fully operates to complete, at RA1365, an obvious path for short-circuiting its lower winding and for impressing ground potential by way of the test wiper 1373 upon the control conductor C1372 of the called line, thereby to mark this line as busy in the usual manner. At RA1368, the relay R1360 opens a point in the circuit, traced hereinafter, for transmitting busy tone current to the receiver provided at the operator's position in the exchange B. At RA1361 and RA1369 and their respective associated working contacts, the relay R1360 prepares the talking circuit to the called substation and in so doing completes a circuit for energizing the signal device provided at the called substation T₃. More particularly, the path traversed by the ringing current may be traced as extending from the ungrounded terminal of the ringing current generator by way of the exchange battery provided in the exchange B, the winding of the slow-acting ring cut-off relay R1300, RA1305, RA1311, RA1361, the wiper 1371, C1381, the bridged ringer

and signal device connected between C1381 and C1383 at the called substation, C1383, the wiper 1372, RA1369 and RA1315 to the grounded terminal of the ringing current source at RA1309. At RA1362, the relay R1360 completes a path extending by way of the condenser 1258 and the line conductor C1261 for conducting a portion of the ringing current through the windings of the repeating transformer 171, whereby the usual ring-back tone signal is reproduced by the receiver provided at the calling operator's position.

When the call is answered at the called substation, a direct current bridge is connected between the line conductor C1381 and C1383 of the called line 33 to complete a circuit, substantially similar to that traversed by the ringing current and traced above, for energizing the slow-acting ring cut-off relay R1300. The relay R1300 operates after an interval to complete, at RA1301, a circuit extending from ground at RA1242 and by way of C1271 for energizing the relay R1310. The last-mentioned relay, upon operating, completes, at RA1314, an obvious holding circuit for itself. At RA1311 and RA1315 and their respective associated resting contacts, the relay R1310 opens two points in the above-traced circuit traversed by the ringing current and two points in the operating circuit for the ring cut-off relay R1300, causing the last-mentioned relay to restore after an interval. Obviously when the ringing current circuit is interrupted at the indicated armature springs of the relay R1310, the path traversed by the ring-back tone current is also interrupted. At RA1311 and RA1315 and their respective associated working contacts, the relay R1310 completes the desired talking connection between the operator's telephone set provided in the exchange B and the called substation. When this talking circuit is completed, the relay R1217 is energized in series with the winding of the line balancing impedance element 1219 over a circuit which may be traced as extending from ground at the upper terminal of the winding of R1217, by way of this winding, C1279, RA1315, RA1369, the wiper 1372, C1383, the bridge across C1383 and C1381 at the called substation, C1381, the wiper 1371, RA1361, RA1311, C1261 and the winding of the impedance element 1219 to battery. The current traversing this circuit serves to energize the transmitter provided at the called substation in the usual manner. When energized over this circuit, the relay R1217 operates to complete, at RA1218, an obvious circuit for energizing the battery reversing relay R1220, which latter relay, upon operating its armature springs RA1222, RA1223, RA1225 and RA1226, reverses battery back over the loop extending to the trunk line terminating equipment shown in the upper portion of Fig. 7. More particularly, when the battery reversing relay R1220 operates, the direction of current flow through the upper winding of the relay R1290 is reversed and this differentially wound relay operates to open, at RA1291, a point in the circuit for energizing the supervisory lamp associated with the link line, as, for example, the line 552, utilized by the operator in the exchange B to establish a jumper connection between the calling and called talking circuits. The resulting deenergization of the indicated supervisory lamp indicates to the operator in the exchange B that the connection desired between the calling and called parties is fully established.

As indicated previously, the above-mentioned jumper connection comprising one of the link lines, as, for example, the line 552, is usually completed by the operator following the receipt of the ring-back tone signal in the manner just explained. If the indicated link line is utilized to set up the desired jumper connection, the two connect switches 607 and 757 are operated to their respective off-normal positions. Following the operation of the two switches 607 and 757, the operator may return the two call and answer switches 619 and 764 to their respective normal positions to disconnect her telephone set from the established connection. When the operator actuates the switch 607 to its off-normal position, the springs 613 are closed to complete an obvious alternative circuit for energizing the line busy lamp 648; the springs 614 and 615 are opened to open a further point in the previously traced circuit for energizing the line signal lamp 649, and the springs 615 and 616 are closed to prepare a circuit, described hereinafter, for energizing the supervisory lamp 511 individually associated with the link line 552. At the springs 610 and 611, a circuit is prepared for energizing the relay R640.

As indicated previously, the control apparatus embodied in the incoming connector switch shown in Figs. 12 and 13 is so arranged that it may be utilized to repeat a third series of impulses dialed at the operator's position to the station selecting apparatus associated with a selected called line of the multiplex type. As explained above, if a line of this character is to be selected by the incoming connector switch, the off-normal springs 1398 are not closed during the vertical or rotary movement of the wipers embodied in the Strowger switching mechanism 1370. Also, the contacts of the level associated with the wiper 1374 are left unwired so that the alternative operating circuit for the relay R1304 is not completed during movement of the switch wipers. Accordingly, the relay R1304 is not energized and occupies its restored position at the time the line switching relay R1360 operates in the manner explained above. With the relay R1304 in its restored position, the relay R1360, upon operating, completes a path for impressing negative battery potential upon the positive side of the selected called line, this path extending from the negative terminal of the exchange battery provided in the exchange B by way of the resistor 1260, RA1237, C1276, RA1309, RA1315, RA1369 and the wiper 1372 to the positive side of the selected called line. At RA1365, the relay R1360, upon operating, connects the control conductor of the selected called line to ground. When ground potential is applied to this control conductor, the station selecting apparatus associated with the called line is seized and conditioned to respond to negative battery pulses transmitted thereto over the positive side of the line. Upon operating, the relay R1360 also functions to prepare the above-traced circuits for projecting ringing current over the called line and for returning the usual ring-back tone signal to the calling operator. At RA1365, the relay R1360 connects the control conductor of the selected line to ground, whereby the station selecting apparatus associated with the called line is seized and conditioned to respond to negative battery pulses transmitted thereto over the positive side of the line. At the beginning of the first impulse of the third series of impulses transmitted to the incoming connector switch, the line 75

relay R1235 restores to open, at RA1237, a point in the path just traced by way of which negative battery potential is impressed upon the positive side of the selected line. Upon restoring, the relay R1235 also completes an alternative circuit for energizing the relay R1335, this circuit extending from ground at RA1236 by way of RA1243, RA1247, RA1204, C1272, RA1326, the winding of R1335, RA1366 and the resistor 1255 to battery. When energized over this circuit, the relay R1335 operates to complete, at RA1337, the operating circuit for the relay R1340, which latter relay, in turn, operates to complete, at RA1342, the operating circuit for the relay R1350. When the relay R1350 operates, it prepares a circuit, traced hereinafter, for energizing the lower winding of the busy test relay R1320. During each succeeding impulse of the third series of impulses dialed at the calling operator's position, the line relay R1235 alternately restores and reoperates so that a corresponding series of negative battery pulses is transmitted over the positive side of the selected line to the station selecting apparatus associated with the line. This station selecting apparatus responds to the negative battery pulses by selecting the particular called substation desired by the calling subscriber and by associating the apparatus provided at the substation with the called line for use in communicating over the connection. During this series of impulses, the relay R1335, due to its slow-to-release characteristic, remains operated to maintain the two relays R1340 and R1350 operated. Shortly following the end of the digit and with the line relay R1235 in its operated position, the relay R1335 restores to open the operating circuit for R1340 and to complete the above-mentioned circuit for energizing the busy test relay R1320, this latter circuit extending from ground at RA1365 by way of RA1352, RA1353, RA1336 and the lower winding of R1320 to battery. Upon operating, the relay R1320 prepares, at RA1323, a holding circuit for itself, which holding circuit is completed in response to the subsequent sequential restoration of the two relays R1340 and R1350 and extends from ground at RA1241 by way of RA1212, C1268, RA1313, RA1323, RC1354, RA1353, RA1336 and the lower winding of R1320 to battery. At RA1326, the relay R1320 opens a point in the above-traced operating circuit for the relay R1335 and, at RA1327, it prepares a point in the circuit for energizing the release magnet 1208. At RA1325, the relay R1320 completes an obvious path for short-circuiting the lower winding of the relay R1340, thereby to render the last-mentioned relay slow to release. At RA1328, the relay R1320 shunts the pulsing springs associated with RA1237, thereby to prevent any further negative battery pulses from being transmitted to the station selecting apparatus associated with the selected called line. At RA1322, the relay R1320 opens a point in the operating circuit for the relay R1360 and prepares a point in the operating circuit, traced hereinafter, for the relay R1210. At RA1321, the relay R1320 completes the above-traced path for connecting the ungrounded terminal of the ringing current source provided in the exchange B to the negative side of the called line and, in so doing, completes the above-traced path by way of which the usual ring-back tone signal is transmitted to the calling operator. The connection of the ringing current source to the negative side of the called line results in the

energization of the signal device provided at the called substation.

When the call is answered at the called substation, ground potential is impressed upon the negative side of the called line to complete the above-traced circuit for energizing the ring cut-off relay R1380. Upon operating, the ring cut-off relay R1380 completes the above-traced operating circuit for the control relay R1310. The relay R1310 now operates to complete its locking circuit, as traced above, and to complete the loop circuit to the called substation, all in the manner previously explained. At RA1311, the relay R1310 disconnects the ungrounded terminal of the ringing current source from the positive side of the called line, thereby to terminate the ringing operation and the ring-back tone signal. At RA1311, the relay R1310 also opens a point in the circuit for energizing the ring cut-off relay R1380, causing the last-mentioned relay to restore. At RA1313, the relay R1310 opens a point in the above-traced holding circuit for the busy test relay R1320 causing the last-mentioned relay to restore. When the loop circuit to the called substation is completed, the relay R1217 is energized thereover in series with the impedance element 1219, whereby talking battery is supplied to the called substation and the relay R1217 is caused to operate to complete the operating circuit for the battery reversing relay R1220. The resulting operation of the battery reversing relay R1220 causes the supervisory lamp associated with the link line 552 to be extinguished in the manner explained previously. Following the sequential operation of the three relays R1310, R1217 and R1220, in the manner just explained, the desired conversational connection between the calling and called substations is fully established. The manner in which this connection is released is explained hereinafter.

As indicated previously, if a selected called line is tested and found busy by the incoming connector switch shown in Figs. 12 and 13, this switch operates to return busy tone to the calling telephone station. Thus, considering further the call routed by way of this switch to the line 33, if this line is busy at the time the wipers of the rotary switch 1370 are moved into engagement with the contacts terminating the conductors thereof, a circuit is completed for energizing the busy test relay R1320, this circuit extending by way of the grounded control conductor C1382, the test wiper 1373, RA1352, RA1353, RA1336 and the lower winding of R1320 to battery. When its lower winding is energized over this circuit, the busy test relay R1320 operates to prepare, at RA1323, the above-traced holding circuit for itself, which circuit is completed in response to the sequential restoration of the three relays R1335, R1340 and R1350 shortly following the end of the second digit dialed at the calling operator's position. As explained previously, when the busy test relay R1320 operates, it opens, at RA1322, a point in the previously traced operating circuit for the switching relay R1360, thereby to prevent the last-mentioned relay from operating to establish a connection to the busy line. At RA1329, the relay R1320 completes a path for effectively connecting the ungrounded terminal of the busy tone current source to the positive side of the calling loop, which path may be traced as extending by way of the condenser 1254, RA1368, RA1354 and RA1329 to the positive line conductor C1279. When this path is completed, the usual busy tone signal is transmitted to the

operator to indicate that the desired line is in use. Upon receiving busy tone, the operator in the exchange B may either initiate the release of the operated switching apparatus, in the manner explained subsequently, or break in upon the previously established connection to the called substation and offer the toll call to the called subscriber.

In order to establish a talking connection to the called line at a time when this line is busy, the operator momentarily actuates the toll offering switch 783 to its off-normal position, thereby to apply ground potential to the positive side of the trunk line 30. When ground potential is impressed upon the positive line conductor C854, the respective series connected lower windings of R1239 and R1235 are short-circuited. As a result, only the upper winding of the differentially wound relay R1230 remains energized and this relay operates to complete, at RA1231, the above-mentioned circuit for energizing the relay R1210, this circuit extending from ground at RA1241 by way of C1265, RA1322, RA1363, C1267, RA1231 and the winding of R1210 to battery. When energized over this circuit, the relay R1210 first closes the "X" contacts associated with RA1213 to complete a path including C1269 and C1278 for short-circuiting the upper winding of the busy test relay R1320, thereby to render the last-mentioned relay slow to release and to prevent the restoration of the busy test relay during the period required for the relay R1210 to complete its operation. At RA1214, the relay R1210, upon fully operating, shunts the operated armature RA1231 of the relay R1230, thereby to complete a locking circuit for maintaining itself energized following the restoration of the relay R1230. Since the toll offering switch is only momentarily operated to its off-normal position, the relay R1230 is caused to restore to open the operating circuit for the relay R1210 shortly following the operation of the last-mentioned relay. At RA1212 and its associated resting contact, the relay R1210 interrupts the previously traced locking circuit for the busy test relay R1320 and, at this same armature and its associated working contact, completes an alternative holding circuit for the relay R1320, this latter circuit extending by way of the grounded control conductor C1382, the test wiper 1373, C1268, RA1212, C1268, RA1313, RA1323, RC1354, RA1353, RA1336 and the lower winding of R1320 to battery. At RA1211 and RA1218, the relay R1210 completes a talking circuit, including the two condensers 1228 and 1229 and the two line conductors C1262 and C1278, to the desired called substation line. It is to be observed that no direct current loop circuit, which might interfere with the release of the operated switch train being utilized in the previously established connection, is completed to the called line. Also, talking battery for energizing the transmitter provided at the called substation is not derived from the incoming connector switch of Figs. 12 and 13, such battery voltage already being impressed upon the called line through the control circuits of the switch train through which the previously established connection extends. After the above-traced talking circuit to the called line is completed, the operator may offer the toll call to the subscriber at the called substation in the usual manner. If the subscriber accepts the call, the operator instructs the parties conversing over the previously established connection to hang up so that the toll connection may be completed. During the release of the

previously established connection extending to the called line, ground potential is removed from the control conductor C1382 and negative battery potential is impressed thereon, so that the busy test relay R1320 is deenergized and restores after an interval determined by its slow-to-release characteristic. Upon restoring, the relay R1320 recompletes, at RA1322, the previously traced operating circuit for the switching relay R1360. At RA1322 and its associated working contact, the relay R1320, upon restoring, opens a point in the previously traced operating and holding circuits for the relay R1210 causing the last-mentioned relay to restore. When the switching relay R1360 operates, it completes the above-traced circuits for projecting ringing current over the selected called line and for returning ring-back tone current to the calling operator's telephone apparatus, and also completes, at RA1365, the above-described path for impressing ground potential upon the control conductor of the called line. The desired conversational circuit is completed, in the manner described previously, when the call is answered at the called substation to cause the sequential operation of the four relays R1300, R1310, R1211 and R1220, followed by the restoration of the relay R1300.

After a connection is established to the called line 33, it will be apparent that the called subscriber may transmit a recall signal to the operator in the exchange B by operating his switch hook momentarily to open the loop circuit extending to the called substation one or more times. Each time this loop circuit is opened, the three relays R1211, R1220 and R790 are caused sequentially to restore in the order named, and the last-mentioned thereof, upon restoring, completes the previously traced circuit for energizing the supervisory lamp 511. Conversely, each time the loop circuit extending to the called substation is recompleted, the relays R1211, R1220 and R790 reoperate in the order named to cause the lamp 511 to be extinguished. Thus, if the loop circuit extending to the called substation is repeatedly opened and closed, the lamp 511 is intermittently energized to give the usual operator recall signal.

The release of the established connection routed through the operator's position in the exchange A and through the operator's position in the exchange B to a substation line terminating at the last-mentioned exchange is partially under the control of the operator in the exchange B and partially under the control of the operator in the exchange A. Thus, if the called subscriber is the first to hang up, the connection is released under the supervision of the operator in the exchange B. More particularly, when the connection is cleared out at the called substation, the relays R1211, R1220 and R790 are caused to restore in the order named and the last-mentioned thereof recompletes, at RA791, the previously traced circuit for energizing the supervisory lamp 511. The resulting continuous illumination of this lamp indicates to the operator in the exchange B that the connection has been cleared out at the called substation. To release the connection, the operator in the exchange B restores the two switches 607 and 757 to normal. The release of the operated switching equipment by way of which the connection is routed to the called subscriber's line is initiated when the operator returns the switch 757 to its normal position to cause the restoration of the relay R795, in the manner explained pre-

viously. This relay, upon restoring, opens the loop circuit extending to the incoming connector switch of Figs. 12 and 13 whereby the line relay R1235 is caused to restore. Upon restoring, the relay R1235 opens, at RA1236, the operating circuit for the slow-to-release hold relay R1240, which latter relay restores, after an interval, to open, at RA1241, a point in the operating circuit for R1245 and a point in the common portion of the holding circuits for the relays R1320 and R1360, causing the one of these relays which is operated to restore. At RA1242, the relay R1240 opens a point in the previously traced holding circuits for the relays R1304 and R1310. At RA1244, the relay R1240 completes the circuit for energizing the release magnet 1208, this circuit extending from ground by way of the resistor 1238, RA1244, RA1205, the off-normal springs 1207 and the winding of the magnet 1208 to battery. The resulting operation of the release magnet 1208 causes the wipers of the Strowger switching mechanism 1370 to be returned to normal in the usual manner, at which time the springs 1207 are opened to interrupt the release circuit just traced. When the wipers of the switching mechanism 1370 are returned to normal, the incoming connector switch illustrated in Figs. 12 and 13 is fully released and is conditioned for further use.

The operator in the exchange B, in order to signal the operator in the exchange A that the connection is ready to be released, momentarily operates the ringing key 632 to its off-normal position, thereby to prepare the previously traced circuit for projecting ringing current over the trunk line 12 to the equipment shown in Fig. 4 and to complete, at the springs 643, the circuit for energizing the relay R645. When the relay R645 operates, it connects the line conductors of the trunk line 12 to the ringing current source provided in the exchange B, whereby ringing current is caused to flow over the trunk line 12 and to traverse the windings 476 and 477 of the repeating transformer 475. The resulting induced voltages developed in the winding 480 serve to energize the ring-up relay conventionally provided in the operator's cord circuit which is now connected to the repeating transformer 475 through the jack 482. This ring-up relay, upon operating, serves to energize the supervisory signal lamp individually associated with the cord circuit being used, so that the operator in the exchange A is apprised that the connection routed by way of the cord circuit is ready for release. The operator in the exchange A may then release the trunk line terminating apparatus shown in Fig. 4 by withdrawing the plug terminating the cord circuit from the call and answer jack 482.

If the connection as established in the manner just described is released at the calling end thereof before the called subscriber hangs up, the operator in the exchange A supervises the release of the connection. Thus, upon receiving the usual disconnect signal, the operator in the exchange A may signal the operator in the exchange B by projecting ringing current over the trunk line 12, in the manner explained previously, to energize the alternating current relay R630. This relay, upon operating, opens, at RA631, a point in the holding circuit for the relay R635, which latter relay, upon restoring, completes, at RA639, a circuit extending by way of the switch springs 615 and 616 for energizing the supervisory lamp 511. At RA636, the relay

R635, upon restoring, completes a circuit for energizing the relay R640, this circuit extending from ground at RA636 by way of the springs 611 and 612 and the winding of R640 to battery. Upon operating, the relay R640 completes, at RA641, a holding circuit for itself and prepares a circuit for energizing the relay R635. After receiving the disconnect signal, the operator in the exchange B may initiate the release of the link line 552, the trunk line terminating apparatus shown in the upper portion of Fig. 7, and the incoming connector switch shown in Figs. 12 and 13, in the manner explained previously. During the release of this equipment, the operated switch 601 is returned to normal, at which time the springs 611 and 612 are closed to complete the above-mentioned alternative operating circuit for the relay R635, this circuit extending from ground at RA636 by way of RA641, the switch springs 611 and 612, RA631 and the winding of R635 to battery. When the relay R635 operates, it completes, at RA638, its holding circuit and opens, at RA638, a point in its alternative operating circuit and a point in the holding circuit for the relay R640, causing the last-mentioned relay to restore. Thus, the apparatus terminating the trunk line 12 in the exchange B is restored to its normal condition.

Subsection B.—Call initiated at the operator's position in the exchange A and routed to the exchange B when the operator in the exchange B is off duty.

As pointed out previously, when the operator in the exchange B leaves her position or goes off duty, the transfer switch 800 is operated to its off-normal position and the transfer switch 483, provided at the operator's position in the exchange A, is also operated to the off-normal position shown in the drawings, whereby toll calls routed between the two exchanges A and B are under the supervision of the operator located in the exchange A. To initiate a call over the trunk line 12 at a time when the operator in the exchange B is off duty, the operator in the exchange A inserts the plug terminating her cord circuit in the answer jack 482, thereby to complete the previously traced circuit for energizing the relay R460. Upon operating, this relay completes, at RA463, a holding circuit for itself and completes, at RA461, the previously traced circuit for energizing the relay R465 in parallel with the slow-to-operate relay R445 and the supervisory lamp 492. The relay R465, upon operating, connects the line conductors C413 and C414 of the trunk line 12 to opposite terminals of the alternating current source provided in the exchange A and opens, at RA467, a point in the operating circuit for the relay R460. The relay R445, upon operating, completes, at RA466, the operating circuit for the slow-to-release relay R430, which latter relay, in turn, operates to complete, at RA432, the operating circuit for the relay R440. The relay R440, upon operating, completes, at its three contact springs RA441, RC442 and RC443, the operating circuit for the slow-to-operate relay R433. The relay R433 operates, after an interval, to open, at RA436, a point in the operating circuit for the relay R405, and to complete, at RA437 and RA438, the previously traced holding circuit for the relay R440. When its operating circuit is opened by the relay R430, the relay R405 restores to disconnect the line conductors of the trunk line 12 from the alternating current source provided in the ex-

change A, thereby to terminate the seizing pulse of alternating current transmitted over the trunk line 12.

With the transfer switch 800 occupying its off-normal position, the alternating current pulse mentioned above is transmitted by way of the trunk line 28 to the repeater illustrated in Figs. 10 and 11 and the control apparatus embodied in this repeater responds by seizing the incoming connector switch shown in Figs. 12 and 13. More particularly, when the relay R405 operates, the alternating current relay R1115 is energized over a circuit which may be traced as extending from one terminal of the alternating current source provided in the exchange A by way of RA411, RA408, C413, the switch springs 801 and 803, C841, RA1141, RA1121, the winding 1178, the condenser 1177, the winding of R1115, the winding 1179, RA1122, C842, the switch springs 806 and 804, C414, RA408 and RA412 to the opposite terminal of the alternating current source. The relay R1115 now operates to complete, at RA1117 and its associated working contact, a circuit extending by way of C1090, RA1037' and RA1056 for energizing the upper winding of the relay R1050. The relay R1050, which is of the two-step type, partially operates to close the "X" contacts associated with RA1054 and thereby complete a path short-circuiting its lower winding when its upper winding is energized over the circuit just traced. At the end of the alternating current pulse transmitted by way of the trunk lines 12 and 28 to the repeater of Figs. 10 and 11, the alternating current relay R1115 restores to open, at RA1117, a point in the path short-circuiting the lower winding of R1050, permitting the two windings of the last-mentioned relay to be energized in series. The relay R1050 now completes its operation to prepare, at RA1056, a circuit, traced hereinafter for energizing the two relays R1060 and R1170. At RA1057, the relay R1050 completes a circuit for energizing the upper winding of the relay R1065 in parallel with the lower winding of the relay R1130, one branch of this circuit extending from ground at RA1057 and through the upper winding of R1065 to battery and the other branch extending by way of C1092, RA1154 and the lower winding of R1130 to battery. At RA1058, the relay R1050 completes a circuit for energizing the slow-to-release relay R1165, this circuit extending from ground at RA1058 by way of C1095, RA1171, RA1151 and the winding of R1165 to battery. The two relays R1130 and R1165 are caused to operate when energized over their respective operating circuits as traced above. The relay R1068, on the other hand, does not operate when its upper winding is energized in response to the operation of R1050, it being so wound that it only operates when its two windings are cumulatively energized. At RA1052, the relay R1050, upon operating, completes a path extending by way of RA1001 for impressing ground potential upon the control conductor C1552, thereby to guard the repeater of Figs. 10 and 11 against seizure by one of the numerical switches provided in the exchange B. At RA1053, the relay R1050 prepares a point in the common portion of the respective holding circuits for the two relays R1012 and R1020. At RA1051, RA1055 and RA1059, the relay R1050 completes a loop circuit to the incoming connector switch shown in Figs. 12 and 13, whereby the last-mentioned switch is seized and conditioned, in the manner explained previously, to respond to impulses transmitted thereto from the

calling operator's position and by way of the repeater illustrated in Figs. 10 and 11. More particularly, this loop circuit may be traced as extending from ground by way of RA1254, the lower winding of R1235, the lower winding of R1230, RC1227, RA1228, RA1206, C854, the switch springs 821 and 823, C847, RA1059, C1096, the winding 1178, C1085, the resistor 1067, the lower winding of R1066, RA1055, C1087, RA1163, the winding 1174, C1078, RA1051, C846, the switch springs 818 and 816, C853, RA1201, RA1223, RC1224, the upper winding of R1230 and the upper winding of R1235 to battery. The line relay R1235, embodied in the incoming connector switch of Figs. 12 and 13, operates when energized over this circuit and initiates the relay operations described previously in section 7, subsection D of this specification, whereby the relay equipment embodied in the incoming connector switch is conditioned to respond to impulses transmitted thereto over the loop circuit just traced. With the battery reversing relay R1220, embodied in the incoming connector switch, occupying its restored position, the direction of current flow over the loop circuit extending to this switch is such that the two windings of the relay R1065 are differentially energized and as a result the relay R1065 remains in its restored position.

As indicated above, the relay R1165 operates in response to the operation of R1050 and, upon operating, prepares, at RA1166, a circuit for energizing the relay R1150. At RA1167, the relay R1165 prepares a holding circuit for itself. At RA1168, the relay R1165 opens a point in an alternative circuit, traced hereinafter, for energizing the lower winding of the relay R1130. The relay R1130 also operates in response to the operation of the relay R1050 and, upon operating, initiates the sequential operation of the three relays R1100, R1105 and R1110 and the operation of the minor switch 1070, all in the manner explained previously with reference to the repeater shown in Figs. 17 and 18. The trunk line terminating equipment shown in Fig. 4, the repeater of Figs. 10 and 11 and the incoming connector switch shown in Figs. 12 and 13 are now conditioned to respond to operation of the dialing device provided at the calling operator's position, it being understood that the calling plug 474 is inserted in the jack 473 before the dialing operation is started. When the plug 474 is inserted in the jack 473, a circuit is completed, at the springs 491, for energizing the two windings of the pulsing relay R410 in series with the two windings of the differentially wound relay R415, this circuit extending from ground at the upper terminal of the lower winding of R410, by way of this winding, the lower winding of R415, the ring contacts of the jack 473 and the plug 474, the pulsing springs 491, the tip contacts of the plug 474 and the jack 473, RA464, RA439, the upper winding of R415 and the upper winding of R410 to battery. The differentially wound relay R415 does not operate when its two windings are energized over this circuit. The pulsing relay R410, on the other hand, operates to open, at RA411 and RA412, two points in the circuit by way of which alternating current is projected over the trunk line 12. During each back stroke of the dial embodied in the calling device 489, the control springs 490 are closed to complete a circuit extending by way of the sleeve contacts of the plug 474 and the jack 473 and RA447 for energiz-

ing the relay R405, which relay operates to prepare the above-traced circuit for projecting alternating current by way of the trunk line 12 to the repeater shown in Figs. 10 and 11. During each return movement of the dial embodied in the calling device 489, the pulse springs 491 are opened one or more times depending upon the number of impulses making up the particular digit dialed. Each time the springs 491 are opened, the pulsing relay R410 is deenergized and restores to complete, at RA411 and RA412, the circuit for projecting alternating current over the trunk line 12. Thus, alternating current impulses are transmitted by way of the trunk lines 12 and 28 to the repeater illustrated in Figs. 10 and 11. Obviously, at the end of each digit, when the control springs 490 are opened in the usual manner, the relay R405 is deenergized and restores to reconnect the line conductors of the trunk line 12 to the line terminals of the repeating transformer windings 478 and 477.

The control apparatus embodied in the repeater shown in Figs. 10 and 11 responds to the alternating current impulses transmitted thereto in the manner just explained by arresting the operation of the minor switch 1070 and by repeating the impulses over the trunk lines 29 and 30 to the incoming connector switch shown in Figs. 12 and 13. Thus, at the beginning of the first impulse of the first series of impulses dialed at the calling operator's position in the exchange A, the alternating current relay R1115 operates to complete the above-mentioned circuit for energizing the winding of R1060 in parallel with the lower winding of R1170, this circuit extending from ground at RA1117 by way of C1090, RA1037, RA1056 and C1089 to RA1164 where it divides, one branch extending through the lower winding of R1170 to battery and the other branch extending by way of C1088 and the winding of R1060 to battery. When energized over this circuit, the slow-acting relay R1060 operates to shunt the lower winding of R1065, the resistor 1067 and the two windings 1174 and 1175 of the repeating transformer 1173 from the loop circuit extending to the incoming connector switch of Figs. 12 and 13, thereby to enhance the response of the line relay R1235 to the impulses transmitted over the indicated loop circuit. More particularly, with the relay R1050 operated, the loop circuit is altered so that it may be partially traced as extending from the trunk line conductor C846 by way of RA1051, RA1062, C1081, RA1163, C1087, RA1058, RA1063, C1088, C1086 and RA1059 to the opposite trunk line conductor C847. Due to its slow-to-release characteristic, the relay R1060 remains operated during the impulses of each series and only restores shortly following the last impulse of each 60 impulse series. The relay R1170 operates when its lower winding is energized in parallel with the relay R1060 over the circuit just traced and, upon operating, prepares, at RA1173, a circuit for energizing its upper winding. At RA1172, the relay R1170 completes a path for short-circuiting the lower winding of R1160, which path may be traced as extending from ground at RA1058 by way of C1095, RA1172, the lower winding of R1160, RA1164, C1089, RA1058, RA1037 and C1080 back to ground at RA1117. At RA1171, the relay R1173 opens a point in the above-traced operating circuit for the slow-to-release relay R1165 and completes a circuit for energizing the relay R1150, this latter circuit extending from ground at RA1058 by way of C1085, RA1171, RA1166 and the wind-

ing of R1150 to battery. The relay R1150, upon operating, completes, at RA1152, an obvious holding circuit for itself and opens, at RA1151, a further point in the operating circuit for the relay R1165. At RA1153, the relay R1150 prepares a holding circuit, traced hereinafter, for the slow-to-release relay R1165. At RA1155, the relay R1150 prepares an alternative operating circuit for the relay R1130. At RA1154, the relay R1150 opens a point in the above-traced operating circuit for the relay R1130. Thereafter, and during the portion of the next operating cycle of the three relays R1100, R1105 and R1110, when the first two thereof are restored, the holding circuit for the relay R1130 is opened, causing this relay to restore to arrest the cyclic operation of the three enumerated relays and the operation of the minor switch 1070. At RA1131 and its associated resting contact, the relay R1130, upon restoring, completes a circuit extending by way of C1084 and the closed off-normal springs 1074 for energizing the release magnet 1073 embodied in the minor switch 1070, it being pointed out that the springs 1074 are closed in the usual manner when the wiper 1071 is moved to its first off-normal position. Thus, the wiper 1071 of the minor switch 1070 is returned to its home position at which time the off-normal springs 1074 are opened to interrupt the operating circuit for the release magnet 1073.

At the end of the first alternating current pulse, representing the open circuit period of the first impulse dialed at the calling operator's position, the relay R1115 restores to interrupt, at RA1117 and its associated working contact, a point in the above-traced circuit for energizing the winding of R1060 in parallel with the winding of R1170 and a point in the above-traced path short-circuiting the lower winding of the relay R1160. At RA1117 and its associated resting contact, the relay R1115 completes a holding circuit for the operated slow-to-release relay R1165, this holding circuit extending from ground by way of RA1117, RA1153, RA1167, and the winding of R1165 to battery. When the path short-circuiting the lower winding of the relay R1160 is interrupted, the lower winding is energized in series with the lower winding of the relay R1170 over a circuit extending from ground at RA1058 by way of C1095, RA1172, the lower winding of R1165 and the lower winding of R1170 to battery. The relay R1160 operates when its lower winding is energized over this circuit and, upon operating, completes, at RA1162, an obvious path for short-circuiting its upper winding, thereby to render itself slow to release. At RA1164, the relay R1160 opens a point in the above-traced circuit for energizing R1160 in parallel with the lower winding of the relay R1170. At RA1161, the relay R1160 completes the above-mentioned circuit for energizing the upper winding of R1170. The two windings of the last-mentioned relay are differentially wound and, hence, when its two windings are both energized, the relay R1170 restores to open, at RA1173, a point in the circuit for energizing its upper winding and, at RA1172, a point in the circuit for energizing its lower winding in series with the lower winding of R1160. Thereafter, and when the release period of the relay R1160 is ended, this relay restores to open, at RA1161, a further point in the circuit for energizing the upper winding of R1170 and to open, at RA1162, the path short-circuiting its own upper winding. At RA1164, the relay R1160, upon restoring, reprepares the

above-traced circuit for energizing the relay R1060 in parallel with the lower winding of the relay R1170. During each succeeding impulse of each digit dialed at the calling operator's position, the two relays R1170 and R1160 interact in the manner just explained, and the last-mentioned thereof functions to repeat the impulse to the incoming connector switch shown in Figs. 12 and 13. Thus, each time the relay R1160 operates, it opens, at RA1163, a point in the above-traced loop circuit extending by way of the two windings of the line relay R1235, causing this line relay to restore. During the interdigit pause between each pair of digits and at the end of the last digit dialed at the calling operator's position, the relay R1060 restores to include the transformer windings 1174 and 1175, and the lower winding of the relay R1060 in the loop circuit extending to the incoming connector switch of Figs. 12 and 13. The incoming connector switch of Figs. 12 and 13 responds to the alternate restoration and operation of the line relay R1235 by selecting the particular line desired by the calling operator located in the exchange A. From this point on, the manner in which the connection may be routed to a subscriber's line terminating at any one of the exchanges B, C, D and E is exactly the same as described previously in this section and Section 7 of this specification. As explained previously, if the call is ultimately routed to an idle subscriber's line and the call is answered at the called substation, battery is reversed over the line conductors of the trunk line 30 incoming to the connector switch of Figs. 12 and 13. Thus, if the connection is routed to a substation line terminating at the exchange B, the called line is selected directly by the indicated incoming connector switch of Figs. 12 and 13, and, when the call is answered at the called substation, the battery reversing relay R1220 is caused to operate to reverse battery back over the conductors of the trunk line 30. On the other hand, if the connection is routed to a substation line terminating at the exchange C, in the manner explained in Section 7, Subsection D, the incoming connector switch of Figs. 12 and 13 switches the loop circuit through to a repeater, as, for example, the repeater shown in Figs. 17 and 18, and battery is reversed over the conductors of the trunk line 30 in response to the operation of the battery reversal relay such, for example, as the relay R1712 embodied in the repeater. In any case, the exchange battery is reversely connected to the conductors of the trunk line 30 when the call is answered at the called substation, thereby to reverse the direction of current flow through the lower winding of the relay R1065. Thus, the two windings of the relay R1065 are cumulatively energized and the relay operates. Upon operating, the relay R1065 completes, at RA1066, a circuit for energizing the slow-acting relay R1100, this circuit extending from ground at RA1117 by way of C1091, RA1066 and its associated working contact, RA1016 and its associated resting contact, RA1036, C1082, RA1112 and the winding of R1100 to battery. Upon operating, the relay R1100 prepares, at RA1104, the previously traced operating circuit for the relay R1105; completes, at RA1103, the operating circuit for the relay R1120; and completes, at RA1102, the operating circuit for the relay R1140. The relay R1120, upon operating, disconnects the conductors of the trunk line 28 from the line terminals of the transformer wind-

ings 1178 and 1179. The relay 1140, upon operating, completes, at RA1142, the operating circuit for the relay R1105 and connects the line conductors of the trunk line 28 to the alternating current source provided in the exchange B. The relay R1105, upon operating, completes the operating circuit for the relay R1110 which latter relay, in turn, operates to open, at RA1112, the operating circuit for the relay R1100. The relay R1105, upon operating, also completes, at RA1108, a circuit for energizing the lower winding of the battery reversing relay, R1012, this circuit extending from ground at RA1155 by way of RA1134, R1108, C1093, RA1023, RA1017 and the lower winding of R1012 to battery. When its lower winding is energized over this circuit, the relay R1012 partially operates to complete, at the "X" contacts associated with RA1013, a path extending from ground at RA1053 for short-circuiting its upper winding. When the relay R1110 operates to open the previously traced operating circuit for R1100, the last-mentioned relay restores to open the operating circuit for R1105. The relay R1105 now restores to open, at RA1108, a point in the path short-circuiting the upper winding of R1012. The two windings of R1012 are now energized in series over a circuit extending from ground at RA1053 by way of RA1041, RA1013 and the two series connected windings of R1012 to battery. The relay R1012 now completes its operation to open, at RA1017, a point in the above-traced circuit for energizing its lower winding and to open, at RA1016, a point in the previously traced operating circuit for the relay R1100. Thus, the cyclic operation of the three relays R1100, R1105 and R1110 is confined to a single cycle of operation. When the relay R1100 restores, in the manner just described, to open the operating circuit for the relay R1105, it also opens, at RA1103 and RA1102, respectively, the operating circuits for the two relays R1120 and R1140, causing these two relays to restore. When the relay R1140 restores, it disconnects the conductors of the trunk line 28 from the alternating current source provided in the exchange B, thereby to terminate the pulse of alternating current transmitted by way of the trunk lines 28 and 12 to the trunk line terminating equipment shown in Fig. 4. The relay R1120, upon restoring, shortly following the restoration of the relay R1140, reconnects the conductors of the trunk line 28 to the line terminals of the repeating transformer windings 1178 and 1179, thereby to recomplete the talking circuit between the calling operator's telephone station and the called substation.

The relay R470 operates in response to the alternating current pulse transmitted over the trunk line 12 by operating to complete, at RA472, the previously traced circuit for energizing the lower winding of the relay R450. When its lower winding is energized, the relay R450 partially operates to complete, at the "X" contacts associated with RA453, the previously traced path for short-circuiting its upper winding. At the end of the alternating current pulse, the relay R470 restores to open, at RA472, the path short-circuiting the upper winding of the relay R450 permitting the two windings of the latter relay to be energized in series. The relay R450 now fully operates to open, at RA451, a point in the previously traced circuit for energizing the supervisory lamp 492. At RA452, the relay R450 prepares a point in the circuit for energizing the line signal lamp 493. The deenergized condition of

the supervisory lamp 492 serves to indicate that the desired conversational circuit is fully established.

If the call as initiated at the operator's position in the exchange A, in the manner just described, is routed to a desired subscriber's line and busy tone is returned over the established connection to the operator to indicate that the desired line is busy, the operator may break in upon the previously established connection to the called line and offer the call to the subscriber located at the called substation. To this end, the toll offering switch, comprising the springs 496, is momentarily operated to its off-normal position to complete an obvious path for short-circuiting the series connected lower windings of the two relays R410 and R415, whereby both of these windings are deenergized. With its upper winding alone energized, the differentially wound relay R415 operates to open, at RA416, a point in the previously traced operating circuit for the relay R445 and to complete a circuit for energizing the relay R420, this latter circuit extending from ground at RA461 by way of the switch springs 484, RA416, RA431, RC426, RA425 and the winding of R420 to battery. The relay R420, upon operating, completes, at RA424 and RA425, an obvious holding circuit for itself and thereafter opens, at RA425 and RC426, a point in its operating circuit. At RA423, the relay R420 completes an obvious circuit for energizing the relay R405. At RA421 and RA427, the relay R420 prepares the circuit for projecting alternating current over the trunk line 12 to the repeater shown in Figs. 10 and 11. The relay R405, upon operating, completes this circuit by connecting the trunk line conductors C413 and C414 to opposite terminals of the alternating current source provided in the exchange A. The relay R445, upon restoring, opens, at RA446, the operating current for the relay R430, causing the last-mentioned relay to restore to interrupt, at RA432, the holding circuit for the relay R420. The relay R420 now restores to open, at RA423, the operating circuit for R405 and to interrupt, at RA421 and RA427, two points in the circuit by way of which alternating current is being conducted to the conductors of the trunk line 12, thereby to terminate the pulse of alternating current being transmitted over this trunk line. At RA422, the relay R420 recomplete the previously traced operating circuit for the relay R445, whereby the last-mentioned relay and the relay R430 are caused to reoperate in the order named. The relay R405, upon restoring, reconnects the line conductors of the trunk line 12 to the line terminals of the repeating transformer windings 476 and 471 to reprepare the desired talking circuit to the called subscriber's line. It will be observed that the duration of the alternating current pulse transmitted by way of the trunk line 12, in the manner just explained is primarily determined by the slow-to-release period of the relay R430. This relay is so constructed and arranged that its release period is quite long, whereby the duration of the alternating current pulse is substantially greater than the seizing pulse of alternating current transmitted over the trunk line 12 when the trunk line terminating equipment, shown in Fig. 4, is taken for use, and is substantially shorter than the release pulse transmitted by way of the trunk line 12 when a connection routed by way of the equipment of Fig. 4 is released by the operator. More particularly, the pulse of alternating current just described

substantially exceeds the time interval required for the relay R1165 to restore after its operating and holding circuits are interrupted.

When the pulse of alternating current is transmitted by way of the trunk line 12 to the repeater shown in Figs. 10 and 11, the relay R1115 is energized and operates to complete, at RA1117, the previously traced operating circuits for the two relays R1060 and R1170. At RA1117 and its associated resting contact, the relay R1115 also opens a point in the holding circuit for the relay R1165. Thus, the relay R1165 is caused to restore and, upon restoring, completes, at RA1168, an alternative operating circuit for the relay R1130, this alternative circuit extending from ground at RA1155 by way of RA1168 and the lower winding of R1130 to battery. Upon operating, the relay R1130 initiates the cyclic operation of the three relays R1100, R1105 and R1110 and also the operation of the minor switch 1070, all in the manner previously described. At the end of the pulse of alternating current, the relay R1115 restores to reprepare the holding circuit for R1165 and to interrupt the respective operating circuits for the two relays R1060 and R1170. The slow-acting relay R1060 remains operated for a short time interval following the restoration of the relay R1115 and, with the first-mentioned relay in its operated position, ground potential is impressed upon both line conductors of the trunk line 29 over a path which may be traced as extending from ground at RA1117 by way of RA1153, RA1167 and its associated resting contact, and C1077 to RA1061, where it divides, one branch extending by way of RA1062 and RA1051 to the negative line conductor C846 of the trunk line 29 and the other branch extending by way of C1081, RA1163, C1087, RA1055, RA1063, C1086, C1096 and RA1059 to the positive line conductor C847 of the trunk line 29. After the release period of the relay R1060 is ended, this relay restores to open, at RA1061, a point in the path just traced and to recomplete, at this same armature, a circuit for again energizing the relay R1165, the last-mentioned circuit extending from ground at RA1117 by way of RA1153, RA1167, C1077, RA1061, C1076, RA1151 and the winding of R1165 to battery. When energized over this circuit, the relay R1165 reoperates to open, at RA1167, a point in the circuit just traced and to recomplete, at RA1167 and its associated working contact, the original holding circuit for itself. The relay R1165, upon reoperating, opens, at RA1168, the above-traced alternative operating circuit for the relay R1130. Thereafter and during the period of the next operating cycle of the three relays R1100, R1105 and R1110 when the first two thereof are restored, the holding circuit for the relay R1130 is interrupted. The relay R1130 now restores to arrest the cyclic operation of the enumerated three relays and the operation of the minor switch 1070. Upon restoring, the relay R1130 also completes the operating circuit for the release magnet 1073, whereby the minor switch 1070 is restored to normal.

When ground potential is impressed upon both conductors of the trunk line 12, the switching apparatus, arranged in tandem with the repeater shown in Figs. 10 and 11, operates to cause the desired talking connection to be set up between the operator's telephone set located in the exchange A and the called subscriber's line. Assuming the called line extends to the exchange B, the manner in which the incoming connector switch of Figs. 12 and 13 operates to complete the

desired talking circuit to the busy called line is described in this section, subsection A. On the other hand, if the busy called line is terminated at the exchange C, the manner in which the switch train comprising the repeater shown in Figs. 17 and 18, the repeater shown in Figs. 26 and 27 and the incoming connector switch shown in Figs. 31 and 32 operates to complete the desired talking circuit to the selected called busy line is described in Section 7, Subsection D. Finally, if the busy called line terminates at the exchange E, the manner in which the repeater 1620 and the incoming connector switch, shown in Figs. 24 and 25 operates to set up the desired talking connection to the called line is explained in Section 7, Subsection I. It will be recalled from the descriptions appearing in the indicated preceding portions of the specification that in any case when ground potential is impressed upon both sides of the trunk line 30 incoming to the connector switch of Figs. 12 and 13, the switching apparatus making up the operated switch train responds by establishing a connection to the busy called line which will in no way interfere with the release of the previously established connection. It will further be recalled that, when the previously established connection is cleared out, the connector switch, through which the toll connection is routed and having access to the called line, automatically operates to resignal the called substation and to complete the desired talking connection between the calling operator's telephone set and the called substation when the call is answered.

If the called subscriber desires to re-signal the operator in the exchange A after a talking circuit has been completed between the calling and called substations, he may do so by operating the hook switch provided at the called substation momentarily to open, one or more times, the loop circuit extending to the called station. Each time this loop circuit is momentarily interrupted, the exchange battery connections to the conductors of the trunk line 30 are reversed, with the result that the direction of current flow through the lower winding of the relay R1065 is momentarily reversed and this relay restores for a short time interval. Upon restoring, the relay R1065 completes, at RA1066 and its associated resting contact, the previously traced operating circuit for the relay R1100, which latter relay, in turn, operates to complete the respective operating circuits for the relays R1120 and R1140 and to initiate the sequential operation of the two relays R1105 and R1110. When the relay R1140 operates, it reconnects the conductors of the trunk line 28 to the alternating current source provided in the exchange B, whereby another pulse of alternating current is caused to be transmitted by way of the trunk lines 28 and 12 to the apparatus shown in Fig. 4. The relay R1105, upon reoperating, completes, at RA1108, a circuit for energizing the lower winding of the relay R1120, this circuit extending from ground at RA1155 by way of RA1134, RA1108, C1093, RA1023, RA1017 and the lower winding of R1020 to battery. When its lower winding is energized over this circuit, the relay R1020 partially operates to complete, at the "X" contacts associated with RA1021, a path extending from ground at RA1053 for short-circuiting its upper winding. The relay R1110, upon operating, initiates the sequential restoration of the three relays R1100, R1105 and R1110 in the manner previously explained. When the relay R1105 restores, the

path short-circuiting the upper winding of the relay R1020 is interrupted, permitting the two windings of this relay to be energized in series. The relay R1020 now fully operates to open, at RA1023, a point in the above-traced circuit for energizing its lower winding and to complete, at RA1022, the operating circuit for the slow-to-operate relay R1040. When the relay R1040 operates, it opens, at RA1041, the respective holding circuits for the two relays R1012 and R1020 causing both of these relays to restore. The relay R1020, upon restoring, opens the operating circuit for the relay R1040, causing the last-mentioned relay to fall back. When the relay R1012 restores, it opens, at RA1016, the previously traced operating circuit for the relay R1100, thereby to arrest the cyclic operation of the three relays R1100, R1105 and R1110 and to cause the restoration of the two relays R1120 and R1140. Upon restoring, the relay R1140 disconnects the conductors of the trunk line 28 from the alternating current source provided in the exchange B, thereby to terminate the pulse of alternating current transmitted to the apparatus illustrated in Fig. 4. When, thereafter, the relay R1120 restores, the indicated trunk line conductors are reconnected to the line terminals of the repeating transformer windings 1178 and 1179 to reprepare the talking circuit between the calling and called substations. Following the sequence of operations just described and when the loop circuit extending to the called substation is recompleted, the exchange battery is again reversely connected to the conductors of the trunk line 30 in the manner previously explained, so that the two windings of the relay R1065 are cumulatively energized and this relay reoperates to recomplete, at RA1066, the previously traced operating circuit for the relay R1100. As a result, the relays R1120 and R1140 are caused to reoperate, so that a third pulse of alternating current is transmitted by way of the trunk lines 28 and 12 to the apparatus illustrated in Fig. 4 and the sequential operation of the two relays R1105 and R1110, followed by the sequential restoration of the relays R1100, R1105 and R1110, is initiated. The relay R1105, upon reoperating, recompletes the previously traced circuit for energizing the lower winding of the relay R1012, causing the latter relay to again partially operate to recomplete the path short-circuiting its upper winding. Shortly thereafter, and when the relay R1105 restores, this short-circuiting path is interrupted to permit the two windings of R1012 to be energized in series, at which time the relay R1012 again fully operates to open, at RA1016, the operating circuit for R1100. Thus, further operation of the three relays R1100, R1105 and R1110 is prevented and the two relays R1120 and R1140 are caused to restore to terminate the pulse of alternating current being transmitted to the apparatus shown in Fig. 4 and to recomplete the talking circuit between the calling and called substations. From the foregoing description it will be apparent that each time the subscriber at the called substation actuates the switch hook provided at this substation to its normal position to open the loop circuit and then releases the hook switch so that the loop circuit is recompleted, the control equipment embodied in the repeater of Figs. 10 and 11 operates to transmit two pulses of alternating current by way of the trunk lines 28 and 12 to the apparatus shown in Fig. 4.

The relay R470 responds to the first of the two supervisory pulses of alternating current

transmitted thereto over the trunk line 12, by operating to recomplete, at RA472, the prepared circuit for energizing the lower winding of the relay R455. The relay R455 now partially operates to complete, at the "X" contacts associated with RA457, a path extending from ground at RA462 for short-circuiting its upper winding. Thereafter, and when the relay R470 restores at the end of the alternating current pulse, this short-circuiting path is interrupted at RA472, and the relay R455 fully operates. Upon operating, the relay R455 opens, at RA458, a point in the circuit for energizing its lower winding and completes, at RA456, an obvious circuit for energizing the slow-to-operate relay R465. When the relay R465 operates, it opens, at RA466, a point in the common portion of the holding circuits for the two relays R450 and R455, causing both of these relays to restore. When the relay R455 falls back, it opens, at RA456, the operating circuit for the relay R465, causing the last-mentioned relay to restore to reprepare a point in the respective holding circuits for the two relays R450 and R455. The relay R450, upon restoring, also completes, at RA451, the previously traced circuit for energizing the supervisory lamp 492.

Shortly following the restoration of R465 and when the second supervisory pulse of alternating current is transmitted over the trunk line 12 to the apparatus shown in Fig. 4, the relay R470 again operates to recomplete, at RA472, the previously traced circuit for energizing the lower winding of R450. The relay R450 again partially operates to recomplete the previously traced path short-circuiting its upper winding. At the end of the second supervisory pulse of alternating current, this short-circuiting path is again interrupted, and the relay R450 again assumes its fully operated position to interrupt, at RA451, the circuit for energizing the supervisory lamp 492. Thus, the apparatus illustrated in Fig. 4 responds to the two impulses transmitted thereto in response to the momentary operation of the hook switch provided at the called substation, by completing, for a short time interval, the circuit for energizing the supervisory lamp 492. If the indicated hook switch is operated to its normal position to open the loop circuit extending by way of the called line more than once, the cycle of operations just described is repeated, with the result that the supervisory lamp 492 is intermittently energized. The flashing of this lamp serves to signal the operator that she is being recalled by the subscriber at the called substation, whereupon she may re-enter the connection and converse with the called subscriber to determine the particular service desired.

The release of the connection under consideration is entirely under the control of the operator located in the exchange A. Thus, when the called subscriber hangs up, the terminals of the battery provided in the exchange B are again reversely connected to the conductors of the trunk line 30, with the result that the relay equipment embodied in this repeater operates to transmit another pulse of alternating current by way of the trunk lines 28 and 12 to the apparatus shown in Fig. 4, all in the manner just described with reference to the operation of this apparatus during a flashing recall operation performed at the called substation. The apparatus or equipment shown in Fig. 4 responds to the pulse of alternating current transmitted thereto by operating to recomplete the circuit for energizing the su-

perisory lamp 492. In this case, since the loop circuit extending by way of the called substation is not recompleted following its interruption, only a single pulse of alternating current is transmitted from the repeater of Figs. 10 and 11 to the apparatus shown in Fig. 4 and, hence, the supervisory lamp 492 remains in its energized condition. The continuous illumination of this lamp indicates to the operator that the connection has been cleared out at the called substation and is ready for release. The operator may now withdraw the plug terminating the cord circuit being used from the answer jack 482 to initiate the release of the apparatus shown in Fig. 4 and the repeater shown in Figs. 10 and 11. More particularly, when the operator withdraws the call and answer plug from the jack 482, the relay R460 is deenergized and restores to open, at RA461, a point in the above-traced circuit for energizing the supervisory lamp 492 and a point in the common portion of the holding circuits for the two relays R440 and R445. At RA462, the relay R460 completes a circuit extending by way of RA436 for again energizing the relay R405. The last-mentioned relay now operates to connect the conductors of the trunk line 12 to the alternating current source provided in the exchange A, whereby an alternating current release pulse is transmitted over the trunk line 12 to the repeater 16 illustrated in Figs. 10 and 11. The duration of this pulse is determined by the time required for the relays R440 and R433 to restore. Thus, when the relay R433 is deenergized, its weighted armature RA441 starts to vibrate alternately to engage the contacts RC442 and RC443, thereby periodically to complete the holding circuit for the relay R433. The relay R433 remains operated until the vibration of RA441 is reduced sufficiently to interrupt the holding circuit for R433. When its holding circuit is finally interrupted, the indicated relay restores to open, at RA436, the above-traced operating circuit for the relay R405, causing the last-mentioned relay to restore and disconnect the conductors of the trunk line 12 from the alternating current source provided in the exchange A. Thus, the alternating current release pulse is terminated. When the relay R445 is deenergized in response to the restoration of the relay R460, it restores to open, at RA446, the operating circuit for the relay R430, causing the last-mentioned relay to restore. Following the restoration of the relays R460, R445, R440, R433, R430 and R405 in the manner just explained, the trunk circuit apparatus shown in Fig. 4 is fully released.

The alternating current relay R1115 embodied in the repeater 16 shown in Figs. 10 and 11 responds to the alternating current release pulse transmitted thereto over the trunk line 21 by operating to recomplete, at RA1117 and its associated working contact, the previously-traced circuit for energizing the slow-acting relay R1060 in parallel with the lower winding of the relay R1170. The resulting operation of the two last-mentioned relays is without effect at this time. At RA1117 and its associated resting contact, the relay R1115, upon operating, opens the previously-traced holding circuit for the slow-to-release relay R1165. Since the indicated release pulse is relatively long and exceeds the period required for the relay R1165 to restore following its deenergization, the last-mentioned relay restores to complete, at RA1168, a circuit for energizing the lower winding of R1130, this circuit 75

extending from ground at RA1155 by way of RA1168 and the lower winding of R1130 to battery. When its lower winding is energized over the circuit just traced, the relay R1130 operates to prepare, at RA1131, a holding circuit for itself and the operating circuit for the minor switch operating magnet 1072; to prepare, at RA1133, the operating circuit for the relay R1105; and to complete, at RA1132, the previously-traced operating circuit for the relay R1100. Thus, the cyclic operation of the three relays R1100, R1105 and R1110 and the operation of the stepping switch 1070 are initiated. During the operation of the switch 1070 and when the wiper 1071 is operated to its first off-normal position, the off-normal springs 1074 are closed to prepare the previously-traced circuit for energizing the release magnet 1073. When the wiper 1071 is operated to its third off-normal position, a circuit is completed for energizing the slow-to-release relay R1045, this circuit extending from ground at RA1117 by way of C1090, RA1037, RA1056, C1089, RA1164, C1088, the wiper 1071 and the winding of R1045 to battery. When energized over this circuit, the relay R1045 operates to complete, at RA1049, a holding circuit for itself, which holding circuit may be traced as extending from ground at RA1117 by way of C1090, RA1037, RA1056, RA1049 and the winding of R1045 to battery. At RA1047 and RC1048, the relay R1045 opens a point in the original holding circuit for the relay R1050. At RA1046 and RA1041, the relay R1045 completes an alternative holding circuit for the relay R1050, this alternative holding circuit extending from ground at RA1117 by way of C1090, RA1037, RA1056, RA1049, RA1046, RA1047 and the two series connected windings of R1050 to battery. Following the operation of the relay R1045 and when the alternating current relay R1015 restores at the end of the alternating current release pulse, the above-traced holding circuits for the two relays R1050 and R1045 are interrupted, causing these two relays to restore in the order named. Also, the relay R1065 and the lower winding of R1070 are deenergized in response to the restoration of the relay R1116. When the relay R1050 restores, it opens, at RA1058, a point in the previously-traced holding circuit for the relay R1150 and a point in the previously-traced circuit for energizing the lower winding of R1160 in series with the upper winding of R1170, causing all three of these relays to restore. At RA1155, the relay R1150, upon restoring, opens the above-traced operating circuit for the relay R1130. Thereafter and during the period of the next cycle of operation of the three relays R1100, R1105 and R1110 when the relays R1100 and R1105 are restored, the holding circuit for the relay R1130 is interrupted, causing the last-mentioned relay R1130 to restore. Thus, the cyclic operation of the three enumerated relays and the operation of the stepping switch 1070 are arrested. When the relay R1130 restores, it completes, at RA1131, the previously-traced circuit for energizing the release magnet 1073, whereby the wiper 1071 of the switch 1070 is returned to its home position in the usual manner. During the release of the switch 1070 and when the wiper 1071 reaches its home position, the off-normal springs 1074 are opened to interrupt the circuit for energizing the release magnet 1073. Thus, the repeater 16 illustrated in Figs. 10 and 11 is fully released.

During the release of the repeater shown in

Figs. 10 and 11, the relay R1050 restores to open, at RA1051, RA1055 and RA1059, three points in the loop circuit extending to the incoming connector switch shown in Figs. 12 and 13, whereby the release of this switch is effected in the manner previously explained, provided the connection was routed to a subscriber's line terminating in the exchange B. On the other hand, if the connection was routed by way of the incoming connector switch of Figs 12 and 13 and additional switching equipment to a subscriber's line terminating at one of the exchanges C, D and E, the release of the switch train consisting of this incoming connector switch and the operated switching apparatus connected in tandem therewith is accomplished in the manner set forth in section 7, it being pointed out that the release of the incoming connector switch of Figs. 12 and 13 is started when the repeater immediately following this switch operates to remove ground potential from the control conductor of the trunk line incoming thereto.

SUBSECTION C.—Call routed from an operator's position in the exchange A to a substation line terminating at the exchange F when the operator in the exchange B is off duty.

If the call originating at or routed by way of the operator's position 10 in the exchange A is initiated at a time when the operator in the exchange B is not on duty and is intended for a substation associated with a line terminating at the exchange F, the connection may be routed by way of the trunk lines 12 and 28, the repeater illustrated in Figs. 10 and 11, the trunk lines 29 and 30, the incoming connector switch of Figs. 12 and 13, the trunk line 35, the repeater shown in Fig. 14 and the trunk lines 41 and 42 to the automatic switching equipment provided in the exchange F, and through this equipment to the desired substation line. In this case, the incoming connector switch of Figs. 12 and 13 responds to the line selecting digits dialed at the operator's position by selecting the trunk line 35 extending to the repeater shown in Fig. 14 and by switching the loop circuit through to the indicated repeater so that the windings of the differentially wound relay R1435 and the windings of the line relay R1430 are energized thereover. When this loop circuit is completed, the relay R1430 operates to complete, at RA1432, the operating circuit for the slow-acting relay R1405 and to prepare, at RA1431, the loop circuit extending by way of the trunk lines 41 and 42 to the exchange F. The relay R1405, upon operating, completes, at RA1406, the previously described circuit for energizing the winding of the relay R1400 in parallel with the lower winding of the relay R1420. At RA1407, the relay R1405 completes an obvious path for impressing ground potential upon the control conductors C1376 and C1461, thereby to mark the repeater of Fig. 14 as busy. At RA1407, the relay R1405 also completes the operating circuit for the slow-to-release relay R1415. The relay R1400, upon operating, attracts its armatures RA1401 and RA1402 to connect the conductors of the trunk line 41 to the line terminals of the repeating transformer windings 1451 and 1452, thereby to complete the above-mentioned loop circuit to the exchange F. The polarity of the current traversing this circuit is such that the relay R1420 does not operate. The relay R1415, upon operating, prepares, at RA1416 and RA1417, the previously traced circuit for impressing booster battery potential upon the con-

trol conductor C1461 of the trunk line 37. Following the operation of the relays R1400 and R1415, in the manner just described, the relay equipment embodied in the repeater of Fig. 14 is conditioned to respond to the impulses making up the third and fourth digits dialed at the calling operator's position and repeated thereto through the operation of the relay equipment embodied in the repeater illustrated in Figs. 10 and 11. As pointed out previously, when the above-traced loop circuit extending by way of the trunk lines 41 and 42 is completed, certain of the automatic switching equipment provided in the exchange F is seized and is conditioned to respond to impulses transmitted thereto in the usual manner. As stated in the preceding subsection, the relay R1160 follows the impulses dialed at the calling operator's position and, in the present case, operates to repeat these impulses to the repeater shown in Fig. 14 by opening and closing the loop circuit in which the windings of the line relay R1430 are included. Thus, the line relay R1430 is caused to follow the impulses. More particularly, this relay restores during the open circuit period of each impulse and opens, at RA1431, a point in the above-traced loop circuit extending to the exchange F. The operated switching equipment provided in the exchange F responds to the repeated impulses by routing the connection to the desired called line, in the manner explained in section 7 with reference to the selection of a line terminating at the exchange E. Each time the line relay R1430 restores during impulsion, it also opens, at RA1432, the operating circuit for the hold relay R1405, but the last-mentioned relay, due to its slow-to-release characteristic, remains operated.

If the line selected by the automatic switching equipment provided in the exchange F is tested by this equipment and found busy, the usual busy tone signal is returned over the established connection to the calling operator located in the exchange A. Following the receipt of busy tone, the operator may break in upon the established connection extending to the busy called line and offer the toll call to the subscriber at the called substation in a manner substantially similar to that set forth in the preceding subsection. Thus, the operator, by momentarily operating the toll offering switch comprising the springs 496 to its off-normal position, may cause ground potential to be impressed upon each of the line conductors C853 and C854 of the trunk line 30 extending to the incoming connector switch of Figs. 12 and 13. On the type of call here being considered, these trunk line conductors are connected through to the conductors C1375 and C1377 of the trunk line 35 and, thus, the respective lower windings of the relays R1435 and R1430 are momentarily deenergized when ground potential is impressed upon the conductors of the trunk line 30. When its lower winding is deenergized, the differentially wound relay R1435 operates to complete, at RA1436, an obvious path for impressing ground potential upon the line conductor C849 of the trunk line 41 and also to complete a path extending by way of the winding 1452, the upper winding of the relay R1420, the winding 1451, RA1431 and RA1401 for impressing ground potential upon the opposite line conductor C848 of the trunk line 41. When ground potential is impressed upon the two conductors of the trunk line 41, the relay equipment, embodied in the incoming connector switch having access to the busy called line and located in the exchange F, oper-

ates, in the manner explained above with reference to the incoming connector switch of Figs. 24 and 25, to establish a talking circuit to the selected called line. After this talking circuit is completed, the operator in the exchange A may offer the toll call to the subscriber at the called substation and, if the call is accepted, instruct the two parties conversing over the previously established connection to hang up. When the previously established connection including the called line is released, the incoming connector switch, located in the exchange F and by way of which the connection is routed from the operator's position in the exchange A to the called line, operates to resignal the called substation and to complete the desired talking circuit to the called line when the call is answered.

In any case, when the call is answered at the called substation, the terminals of the battery provided in the exchange F are reversely connected to the conductors of the trunk line 42 to reverse the direction of current flow through the upper winding of the relay R1420, with the result that this relay now operates to complete, at RA1422, the circuit for energizing the relay R1410 and to complete, at RA1421, the circuit for energizing the battery reversing relay R1440. Upon operating, the last-mentioned relay reverses battery back over the trunk lines 35, 30 and 29 to the repeater shown in Figs. 10 and 11, causing the control apparatus of this repeater to operate to transmit a supervisory pulse of alternating current to the apparatus shown in Fig. 4. The apparatus of Fig. 4 responds to this supervisory pulse of alternating current by opening the circuit for energizing the supervisory lamp 492 in the manner set forth in the preceding subsection. At RA1448 and RA1449, the relay R1440 completes the previously traced path for impressing booster battery potential upon the control conductor C1461 of the trunk line 37, but the completion of this path is without effect on the type of call here being considered. The relay R1410, upon operating, opens, at RA1411 and its associated resting contact, a point in the operating circuit for the relay R1415. At RA1411 and its associated working contact, the relay R1410 completes the previously traced holding circuit for itself. At the end of its release period, the slow-to-release relay R1415 restores to open, at RA1416 and RA1417, a point in the path for impressing booster battery potential upon the control conductor C1461 of the trunk line 37'. At RA1417 and RC1418, the relay R1415, upon restoring, completes a path extending from ground at RA1407 for impressing ground potential upon the indicated control conductor of the line 37', thereby to maintain the repeater shown in Fig. 14 marked as busy in the bank contacts of the local connector switches having access to the trunk line 37'.

After the connection to the called substation is established, the called subscriber may recall the operator in the exchange A by operating the hook switch provided at the called substation repeatedly to open the loop circuit extending to this substation. Each time this loop circuit is opened, the direction of current flow through the upper winding of the relay R1420 is reversed, causing this relay to restore. Conversely, each time this loop circuit is recompleted, the two windings of the relay R1420 are cumulatively energized and the relay reoperates. Upon restoring and re-operating, the relay R1420 opens and closes, at RA1421, the operating circuit for the battery re-

versing relay R1440. Thus, the last-mentioned relay is caused repeatedly to reverse battery back over the loop extending by way of the trunk line 35 to the repeater shown in Figs. 10 and 11. Each time battery is reversed over the last-mentioned loop circuit, the repeater responds, in the manner described in the preceding substation, by transmitting a pulse of alternating current to the apparatus shown in Fig. 4, and this apparatus, in turn, responds to the alternating current pulses by alternately completing and opening the circuit for energizing the supervisory lamp 492. The flashing of this lamp indicates to the operator that she is being recalled by the called subscriber.

The release of the connection just described is entirely under the control of the operator located in the exchange A. Thus, when the subscriber at the called substation hangs up at the end of the conversation, the battery provided in the exchange F is again reversely connected to the conductors of the trunk line 42 to reverse the direction of current flow through the upper winding of the relay R1420. This relay now restores to open, at RA1422, a point in the operating circuit for the relay R1410 and to open, at RA1421, the operating circuit for the relay R1440. The relay R1440, upon restoring, reverses battery back over the trunk lines 35, 30 and 29 to the repeater shown in Figs. 10 and 11, whereby this repeater is caused to operate to transmit a pulse of alternating current to the apparatus shown in Fig. 4. This apparatus responds to the pulse of alternating current by operating to recomplete the circuit for energizing the supervisory lamp 492 and the resulting continuous illumination of this lamp indicates to the operator that the connection is ready for release. The manner in which the apparatus shown in Fig. 4 and the repeater shown in Figs. 10 and 11 are released when the operator withdraws her line connecting plug from the jack 482 is set forth in the preceding subsection. During the release of the repeater and when the relay R1050 restores to open the loop circuit extending through to the repeater shown in Fig. 14, the line relay R1430 restores to open, at RA1431, the loop circuit extending to the operated switch train in the exchange F, thereby to initiate the release of this switch train in the manner described previously with reference to the incoming connector switch shown in Figs. 24 and 25. Upon restoring, the relay R1430 also opens, at RA1432, the operating circuit for the hold relay R1405. The last-mentioned relay restores, after an interval, to open, at RA1406, the circuit for energizing the winding of R1400 and the lower winding of R1420 in parallel. Upon restoring, the relay R1405 also opens, at RA1407, a point in the holding circuit for the relay R1410 and a point in the path by way of which ground potential is impressed upon the control conductors C1376 and C1461 of the trunk lines 35 and 37', respectively. At RA1407 and its associated resting contact, the relay R1405 completes a path extending by way of the resistor 1455 for impressing negative battery potential upon the two control conductors C1376 and C1461, thereby to mark the repeater shown in Fig. 14 as idle in the usual manner. Following the restoration of the relay R1410, all of the relays embodied in this repeater are restored to normal and the repeater is conditioned for further use. Also, when ground potential is removed from the control conductor C1376, the release of the incoming connector switch shown in Figs. 12 and 13 is initiated, the manner in which this switch is

released being set forth in this section, subsection A.

SUBSECTION D.—Extension of a connection from an operator's position in the exchange A through the exchanges D and C to the operator's position in the exchange B.

While calls routed to an operator's position in the exchange A and intended for substation lines necessitating the intervention of the operator in the exchange B are normally routed directly to the operator's position in the exchange B over one of the group of trunk lines including the line 12, the arrangement is such that, if the trunk lines of this group are for some reason out of service, the desired connection may be routed through the switching apparatus provided in the exchanges D, C and B to the operator's position in the last-mentioned exchange. For example, the operator on duty at the position 10 in the exchange A may seize the apparatus schematically indicated at 10_b, the trunk line 13, the repeater 72 and the incoming connector switch 67 by inserting the plug terminating her circuit in the jack embodied in the apparatus 10_a which corresponds to the jack 482. Thereafter, and when the appropriate line selecting digits are dialed at the calling operator's position, the seized incoming connector switch 67 responds by seizing the repeater 66 associated with the trunk line 65 and by switching the calling loop circuit through to the seized repeater. The repeater 66 is thus caused to operate to transmit a seizing pulse of alternating current by way of the trunk line 65 to the distant repeater 57 located in the exchange C. The last-mentioned repeater responds to the seizing pulse of alternating current by seizing the incoming connector switch 56, whereby this incoming connector switch is conditioned to respond to further impulses dialed at the calling operator's position and repeater thereto through the three tandem connected repeaters 72, 66 and 57. Since the incoming connector switch 56 has access to all of the subscribers' lines terminating at the exchange C and is identical in arrangement with the corresponding switch shown in Figs. 31 and 32, it will be obvious that the connection may be routed to any desired substation line terminating at the exchange C without the assistance of the operator in the exchange B. On the call here being considered, however, wherein a connection is desired to the operator's position in the exchange B, the appropriate line selecting digits are dialed at the calling operator's position in the exchange A to cause the incoming connector switch 56 to select a trunk line extending to one of the repeaters in the group including the repeater 50 shown in Figs. 26 and 27. Assuming that the last-mentioned repeater is idle, the incoming connector switch 56 operates to seize the trunk line 62 and to switch the loop circuit extending from the repeater 57 through to the selected repeater 50, shown in Figs. 26 and 27. From this point on, the connection may be routed to the operator's position in the exchange B in the exact manner set forth in Section 8, Subsection B with reference to a call initiated on a line terminating at the exchange C. In the present case, however, since the loop circuit extending to the repeater 50, shown in Figs. 26 and 27, comprises the conductors C2892 and C2993 of the trunk line 62 and also the armature springs controlled by the battery reversing relay R2760, this battery reversing relay, in cooperation with the 75

repeaters 57, 66 and 72 is effective to cause the previously described supervisory pulse of alternating current to be transmitted by way of the trunk line 13 to the apparatus 10_b provided at the calling operator's position, for the purpose of controlling the relay, embodied in this apparatus, which controls the energization of the supervisory lamp individually corresponding to the trunk line 13. The manner in which the five repeaters 24, 50, 57, 66 and 72 and the apparatus 10_b, provided at the calling operator's position, function to control the supervisory lamp associated with the trunk line 13 to give the operator the appropriate supervisory signals will be clearly apparent in view of the preceding description with reference to the manner of controlling the supervisory lamp 492 individual to the trunk line 12 and embodied in the apparatus 10_a shown in Fig. 4. The release of the connection as established between the operator's position in the exchange A and the operator's position in the exchange B, in the manner just described, is primarily under the control of the operator in the exchange A. Thus, when the connection is cleared out at this operator's position, the apparatus diagrammatically illustrated at 10_b and the repeater 72 are released, in the manner described in Section 7—Subsection C with reference to the apparatus shown in Fig. 4 and the repeater shown in Figs. 10 and 11. During the release of the repeater 72, the loop circuit extending from this repeater through the incoming connector switch 67 to the repeater 66 is interrupted, thereby to initiate the release of the repeater 66. In the course of the release of the last-mentioned repeater, the apparatus embodied therein functions to transmit a release pulse of alternating current over the trunk line 65 to the repeater 57 and also to remove ground potential from the control conductor of the trunk line extending between the incoming connector switch 67 and the repeater 66. The incoming connector switch 67 is released in response to the removal of ground potential from the control conductor of this trunk line in the manner described previously with reference to the similar incoming switch shown in Figs. 31 and 32. The repeater 57 responds to the alternating current release pulse transmitted thereto over the trunk line 65 by restoring to normal and by opening the loop circuit extending through the incoming connector switch 56 and by way of the trunk line 62 to the repeater 50 shown in Figs. 26 and 27. The last-mentioned repeater, in turn, operates to transmit a release pulse of alternating current over the trunk line 37 to the repeater 24, illustrated in Figs. 17 and 18, and to remove ground potential from the control conductor of the trunk line 62, thereby to initiate the release of the incoming connector switch 56. When the alternating current release pulse is transmitted over the trunk line 37 to the repeater of Figs. 17 and 18, this repeater is released, and, during its release, opens the loop circuit extending through the operated local finder-connector link provided in the exchange B to the apparatus associated with the trunk line by way of which the connection was routed to the operator's position in the exchange B. For example, if the connection extends through the local finder-connector link of Figs. 19 and 20 and over the trunk line 36 to the trunk line terminating apparatus shown in the lower portion of Fig. 6, the loop circuit extending to this apparatus and including

the windings of the line relay R685 is interrupted during the release of the repeater 24 shown in Figs. 17 and 18. When the indicated line relay restores, it opens the operating circuit for the hold relay R690, causing the latter relay to restore and remove ground potential from the control conductor C851 of the trunk line 36. When ground potential is removed from this control conductor, the release of the operated finder-connector link shown in Figs. 19 and 20 is initiated, the manner in which this link is released being explained in Section 7—Subsection A. When the last-mentioned link is restored to normal, all of the switching apparatus utilized in completing the connection between the operator's position in the exchange A and the operator's position in the exchange B is fully released and ready for further use.

SECTION 10.—CALL ORIGINATING ON A LINE TERMINATING AT THE EXCHANGE E

SUBSECTION A.—Local connection completed between two substations associated with lines terminating at the exchange E

The manner in which a local connection between two substation lines, both extending to the exchange E, is completed and released is exactly the same as set forth in Section 8—Subsection A with reference to the completion of a local connection between two substations associated with lines terminating at the exchange C. Briefly to summarize, when a calling condition is created on any of the lines extending to the exchange E, a switching selector repeater, as, for example, the repeater 80, is assigned to the use of the calling line by the distributor 81, and the assigned switching selector repeater operates to seize one of the trunk lines extending to the exchange B in the manner explained in the next succeeding subsection. When the call is to be extended to a substation line also terminating at the exchange E, however, the seized switching selector repeater operates to release the seized trunk line extending to the exchange C and to seize a local connector switch, such, for example, as the switch 82, when a first digit identifying the call as a local call is dialed at the calling substation. From this point on, the manner in which the connection is routed to the desired substation and is thereafter released is exactly the same as described previously with reference to the local connector switch shown in Fig. 33.

SUBSECTION B.—Toll call originating on a line terminating at the exchange E

If a toll call is initiated on one of the lines extending to the exchange E, such, for example, as the line 76, and the appropriate digits are dialed at the calling substation, a connection is routed to the operator's position in the exchange B or to the operator's position in the exchange A, depending upon the position of the transfer switch 800, through one of the local finder-connector links provided in the exchange B. Thus, if a subscriber at the substation T₂ requires the assistance of a toll operator in completing a desired connection, he may initiate the call in the usual manner by removing his receiver from its supporting hook or cradle, thereby to complete a loop circuit extending to the line circuit 78. The relay equipment embodied in this line circuit now operates to impress ground potential upon the start conductor extending to the distributor 81, whereby the operation of this

distributor is initiated to assign an idle one of the switching selector repeaters to the use of the calling line and to cause the operation of the finder portion of the assigned repeater to seize the calling line. Assuming that the switching selector repeater 80 is assigned to the use of the calling line, when this switch is seized, it operates automatically to select an idle one of the trunk lines extending to the exchange B, and the finder portion thereof operates to seize the calling line. Assuming further that the trunk line 83 is selected by the switching selector repeater 80, immediately this line is seized ground potential is impressed upon the control conductor C2409 and a direct current bridge is connected between the two trunk line conductors C2478 and C2479. When ground potential is impressed upon the control conductor C2409, the relay R2400 is energized over a circuit extending by way of the grounded conductor C2409, RA2432 and the winding of R2400 to battery. When energized over this circuit, the relay R2400 operates to open, at RA2402 and its associated resting contact, one of the multiple paths by way of which ground potential is normally maintained upon the all-switch-busy conductor C2404. At RA2401 and RA2403 and their respective associated working contacts, the relay R2400 connects the conductors C2476 and C2477 of the trunk line 31' to the conductors C2478 and C2479 of the trunk line 83, thereby to extend the loop circuit by way of the trunk line 31' to the line circuit diagrammatically illustrated at 1610 and associated with the trunk line 31'. When this loop is extended to the line circuit 21, the line circuit operates to impress ground potential upon the start conductor C2328 extending to the link distributor shown in Fig. 22. When ground potential is impressed upon this start conductor, the distributor of Fig. 22 operates to assign an idle one of the local finder-connector links to the use of the calling trunk line 31' and to cause the operation of the finder portion of the assigned link to seize the trunk line 31'. Following the operation of the finder portion of the assigned local finder-connector link to seize the indicated trunk line, the control apparatus embodied therein is conditioned to respond to impulses transmitted thereto through the switching selector repeater 80 and over the trunk lines 83 and 31'. The line circuit 21 associated with the trunk line 31', upon operating, also functions to impress ground potential upon the respective control conductors C1683 and C1686 of the trunk lines 31 and 38, whereby the repeater 20 associated with the trunk line 31' is guarded against seizure by one of the connector switches located in the exchange B. From this point on, the manner in which the connection is forwarded to the operator's position in the exchange B or to the operator's position in the exchange A is exactly the same as set forth previously in Section 7 of the specification.

If the call originating at the substation T₂ is routed to the operator's position in the exchange B, the release of the operated switch train is under the control of the calling subscriber. Thus, when the subscriber at the calling substation T₂ hangs up to open the loop circuit extending to the switching selector repeater 80, this repeater restores, in the manner described previously with reference to the similar repeater of Figs. 28 and 29, and, during its release, opens the loop circuit extending by way of the trunk lines 83 and 31'

and the local finder-connector link in the exchange B to the operator's position in the exchange B. When this loop circuit is interrupted, the relay equipment associated with the trunk line extending to the operator's position operates to remove ground potential from the control conductor of this trunk line, whereby the operated local finder-connector link included in the switch train is also released. During the release of this link, ground potential is removed from the control conductor of the trunk line 47 so that the line circuit 21 restores to remove ground potential from the respective control conductors C1686 and C1683 of the trunk lines 38 and 31, permitting these two control conductors to be marked with battery potential as applied thereto through the resistor 1683, whereby the repeater 20 is marked as idle in the bank contacts of the connector switches having access thereto.

If the call originating at the substation T₉ is forwarded to the operator's position in the exchange A, the release of the operated switch train in the exchange B is accomplished in the manner set forth in detail in Section 7—Subsection C.

SECTION 11.—TOLL CALL ORIGINATING ON A LINE TERMINATING AT EXCHANGE F

If a toll call is initiated on one of the lines extending to the exchange F at a time when the operator in the exchange B is on duty such that the transfer switch 800 occupies its off-normal position, the call is routed through the automatic switching equipment provided in the exchange F and over one of the trunk lines extending between the exchanges B and F directly to the operator's position in the exchange B. The indicated trunk lines are of the ring-down type, that is, when one thereof is seized by the automatic switching equipment provided in the exchange F, ringing current is projected thereover for the purpose of energizing the line signal lamp individual to the trunk line in use. Thus, if the trunk line 42 is seized by the switching apparatus provided in the exchange F, ringing current is projected thereover to energize the alternating current relay R750. The path traversed by this ringing current may be partially traced as extending by way of the upper line conductor of the trunk line 42, the switch springs 824 and 825, C839, RA732, RC135, the winding 719, the condenser 754, the winding of R750, RA748, the winding 721, RC136, RA734, C840 and the switch springs 828 and 821 to the lower conductor of the trunk line 42. When energized over this circuit, the relay R750 operates to open, at RA751, the normally closed holding circuit for the slow-to-release relay R755, causing the last-mentioned relay to restore. Upon restoring, the relay R755 opens, at RA756, a further point in its holding circuit and completes, at RA757, a circuit for energizing the line signal lamp 706 individual to the trunk line 42, this latter circuit extending by way of the grounded armature RA757, the filament of the lamp 706, C544 and the winding of R520 to battery. The resulting energization of the lamp 706 indicates to the operator in the exchange B that an incoming call on the trunk line 42 should be answered. As explained previously, if the switch 513 provided at the operator's position occupies its off-normal position, the visual signal, occasioned by the illumination of the line signal lamp 706, is supplemented by the operation of the buzzer 525. To answer the

call, the operator in the exchange B operates the call and answer switch 707 to its off-normal position, thereby operatively to connect her telephone set to the repeating transformer 715 so that a talking circuit is completed to the calling substation. At the springs 711, the circuit is completed for energizing the line busy lamp 760 in parallel with the winding of the relay R745, whereby the busy lamp is energized to indicate the busy condition of the trunk line 42 and the relay R745 is caused to operate. Upon operating, the relay R745 completes, at RA747, a circuit for energizing the upper winding of the relay R740 and completes, at RA748, a loop circuit including the lower winding of R740 and extending to the operated switch train in the exchange F. The direction of current flow over this loop circuit is such that the differentially wound relay R740 operates to open, at RA741, a point in the circuit for energizing the supervisory lamp individually associated with the link line, such, for example, as the line 552, utilized in completing the desired connection. When this loop circuit is completed, the ringing operation is arrested in the usual manner. At RA748 and its associated resting contact, the relay R745 opens a point in the above-traced circuit traversed by the ringing current. Thus, the relay R750 is caused to restore immediately the relay R745 operates. At RA746, the relay R745 completes an obvious operating circuit for the relay R755, causing the last-mentioned relay to reoperate and recomplete its holding circuit at RA758. At RA751, the relay R755 opens the above-traced circuit for energizing the line signal lamp 706 in series with the relay R520, whereby this lamp is extinguished and the operation of the buzzer 525 is arrested. Following the completion of the above-described talking circuit, the operator in the exchange B may converse with the calling subscriber to ascertain the desired substation. In this regard, it will be apparent that the call may be extended from the operator's position in the exchange B to any desired line terminating at the exchanges A, B, C, D and E in the manner set forth in the preceding sections of the specification. In setting up the desired connection, the operator may utilize one of the link lines, such, for example, as the link line 552, to establish the usual link or jumper connection between the talking circuit extending to the calling substation and the talking circuit extending to the called substation. To this end, and if the indicated link line is utilized for this purpose, the key switch 701 is operated to its off-normal position to complete the desired jumper connection. Thereafter, the switch 707 may be restored to its normal position to free the operator's telephone equipment for use in supervising other calls. When the switch 701 is operated to its off-normal position, a circuit is completed, at the springs 704, for maintaining the relay R745 operated until the connection is cleared out. At the springs 703 the circuit is prepared for energizing the supervisory lamp 511 individual to the link line 552. The deenergized condition of this lamp indicates to the operator that the desired connection is fully established. During the release of the connection and when the calling party hangs up, the release of the switch train in the exchange F is initiated. During the release of this switch train, the loop circuit including the resistance 137 and the lower winding of the relay R740 is interrupted. The relay R740 now restores to complete, at RA741, a

circuit extending from ground at RA746 and by way of the switch springs 703 for energizing the supervisory lamp 511, thereby to indicate to the operator that the connection is ready for release. Thereafter and when the operator restores the switch 701 to normal, the holding circuit for the relay R745 is interrupted at the switch spring 704. The relay R745 now restores to open, at RA746, a point in the circuit for energizing the supervisory lamp 511 and, at RA747, a point in the circuit for energizing the upper winding of R740. At RA748, the relay R745 opens a further point in the loop circuit including the trunk line 42 and extending to the exchange F. At RA746, the relay R745 also opens a point in the operating circuit for the relay R755. Thus, the relay equipment associated with the repeating transformer 715 which terminates the trunk line 42, is entirely released.

If the toll call just described is initiated at a time when the operator in the exchange B is off duty, the connection is forwarded to the operator in the exchange A in order that this operator may supervise the completion of the connection. More particularly, with the springs of the transfer switch 800 occupying the positions shown in the drawings, the ringing current which is projected over the trunk line 42 following seizure of this trunk line by the automatic switching equipment located in the exchange F serves to energize the relay R1500. The path traversed by this ringing current may be partially traced as extending by way of one side of the trunk line 42, the switch springs 826 and 824, C848, RA1401, C1457, the winding of R1500, RA1532, the condenser 1522, C1458, RA1402, C849 and the switch springs 829 and 827 to the opposite side of the trunk line 42. When energized over this circuit, the relay R1500 operates momentarily to prepare, at RA1501, a circuit, traced hereinafter, for transmitting a busy tone signal to the calling subscriber and completes, at RA1502, an obvious circuit for energizing the slow-acting hold relay R1510. The relay R1510 now operates to complete, at RA1514, an obvious path for impressing ground potential upon the control conductors C1376 and C1461 of the trunk lines 35 and 37', respectively, thereby to mark the repeater shown in Fig. 14 as busy in the bank contacts of the connector switches having access thereto. When ground potential is impressed upon C1376, the relay R1415 is energized, but the resulting operation of this relay is without effect at this time.

As pointed out previously, the apparatus shown in Fig. 15, in association with the trunk line 43, is provided for the purpose of selecting an idle one of two repeaters in the group including the repeater shown in Figs. 10 and 11 and by way of which connections are routed to the operator's position in the exchange A. Thus, the trunk line 44 extends to the repeater shown in Figs. 10 and 11, whereas, the trunk line 44' extends to a second repeater in the same group. The idle or busy condition of the repeaters respectively terminating the trunk lines 44 and 44' is indicated by the character of the potential impressed upon the respective control conductors of these two trunk lines. Thus, when the repeater shown in Figs. 10 and 11 and terminating the trunk line 44 is busy, ground potential is impressed upon the control conductor C1552, whereas, when this repeater is idle, battery potential is maintained upon the conductor C1552. Similarly, when the repeater terminating the trunk line 44' is idle, battery potential is present upon the control conductor

C1561, which battery potential is replaced with ground potential when the associated repeater becomes busy. Assuming that the repeater shown in Figs. 10 and 11 and terminating the trunk line 44 is idle at the time the call is routed to the trunk selecting apparatus shown in Fig. 15, when the relay R1510 operates, it completes at RA1511, an obvious circuit for energizing the winding of the relay R1530 in series with the upper winding of the relay R1540. The relay R1530 operates when energized over this circuit, but the relay R1540, due to the relatively high resistance of the winding of R1530, is insufficiently energized to operate and remains in its restored position. Upon operating, the relay R1530 completes, at RA1531, an obvious path for connecting the winding of R1500 across the conductors C1457 and C1458 of the trunk line 41, thereby to complete a loop circuit extending back to the operated numerical switch in the exchange F. When this loop circuit is completed, the ringing operation is terminated in the usual manner and the talking circuit is switched through to the line conductors of the trunk line 41. The direct current traversing this loop circuit serves to maintain the relay R1500 energized so that it remains in its operated position. At RA1532 and RA1537 and their respective associated working contacts, the relay R1530, upon operating, completes a loop circuit including the winding of the relay R1520 and extending by way of RA1542, RA1547, C1551 and C1553 to the repeater shown in Figs. 10 and 11. When this loop circuit is completed, the relay R1520 operates to open, at RA1521, a point in the path for transmitting busy tone current back over the talking circuit extending to the calling substation. Also, the completion of this loop circuit results in the operation of the seized repeater to forward the connection to the operator's position in the exchange A, all in the manner described in section 7—subsection C. After the connection has been forwarded to the operator's position in the exchange A, it may be further extended to the desired substation under the supervision of the operator in the exchange A, all in the manner previously explained in section 10 of this specification.

As indicated above, in the event the repeater shown in Figs. 10 and 11 is busy at the time the relay R1510 operates, ground potential is present upon the control conductor C1552 of the trunk line 44 so that the winding of the relay R1530 is short-circuited in response to the operation of R1510. The path short-circuiting the winding of R1530 may be traced as extending by way of the grounded control conductor C1552, RC1545, RA1544, RA1533, RA1512 and the winding of R1530 back to ground at RA1511. By virtue of the completion of this path, the winding of the relay R1530 is not energized, and hence, this relay remains in its restored position. Since the control conductor C1552 is grounded, the upper winding of the relay R1540 is directly energized over a circuit including RC1545, RA1544, RA1533 and RA1512 when the relay R1510 operates. When its upper winding is energized over the circuit just traced, the relay R1540 operates, providing the repeater terminating the trunk line 44' is idle. Upon operating, the relay R1540 completes, at RA1541, the above-described loop circuit extending to the operated switching equipment in the exchange F, thereby to arrest the ringing operation and to complete a direct current circuit for maintaining the relay R1500 energized. At RA1544 and RC1545, the relay

R1540 opens a point in its operating circuit, as traced above, and also a point in the above-traced path short-circuiting the winding of the relay R1530. The relay R1530 is now energized in series with the upper winding of the relay R1540 and operates to complete, at RA1534 and RA1535, a holding circuit for the relay R1540, which holding circuit may be traced as extending from ground at RA1546 by way of RA1534, RA1535, RA1513 and the lower winding of R1540 to battery. With the two relays R1530 and R1540 operated, a loop circuit is completed by way of the trunk line 44' to the repeater at which this trunk line is terminated, whereby this repeater is caused to operate to forward the connection to an operator's position in the exchange A, all in the manner explained previously with reference to the repeater shown in Figs. 10 and 11 and the apparatus shown in Fig. 4. When the last-mentioned loop circuit is completed, the relay R1520 is energized thereover and operates to open, at RA1521, a point in the circuit for transmitting busy tone current back over the talking circuit extending to the calling substation.

As indicated above, if both of the trunk lines 44 and 44' are busy at the time the relay R1510 operates, ground potential is present upon both of the control conductors C1561 and C1552. In this case, the relay R1540 is caused to operate in the manner explained previously to open, at RA1544 and RC1545, the path for short-circuiting the winding of the relay R1530. Since, however, the control conductor C1561 is also grounded, an alternative path extending by way of RA1543 and RA1544 is completed for maintaining the winding of R1530. Thus, the relay R1530 is prevented from operating. With the relay R1530 in its restored position, the relay R1520 cannot operate and, hence, when the talking circuit is switched through to the trunk selecting apparatus shown in Fig. 15 in response to the operation of the relay R1540, the usual busy tone signal is returned to the calling subscriber. More particularly, with the relay R1500 operated and the relay R1520 restored, the ungrounded terminal of the busy tone current source provided in the exchange B is effectively connected to the negative trunk line conductor C1458 over a path extending by way of the condenser 1562, RA1501, RA1521, RA1532 and RA1541. When this path is completed, busy tone current is returned over the talking circuit extending to the calling substation to energize the receiver provided at this substation in the usual manner and thus inform the calling subscriber that the desired connection cannot be obtained.

On the type of call under consideration, the release of the operated switch train in the exchange F and the release of the trunk selecting apparatus shown in Fig. 15 is entirely under the control of the calling subscriber. More particularly, when the calling subscriber hangs up, the operated switch train in the exchange F is released and the loop circuit extending by way of the trunk lines 42, 41 and 43 to the trunk selecting apparatus shown in Fig. 15 is interrupted. When this loop circuit is interrupted, the relay R1500 is deenergized and restores to open, at RA1502, the operating circuit for the relay R1510 and to interrupt, at RA1501, a point in the above-traced path for projecting busy tone current over the negative side of the trunk line 43. The hold relay R1510, upon restoring, opens, at RA1511, RA1512 and RA1513, points in the previously traced operating and holding circuits

for the two relays R1530 and R1540, causing either or both of these relays to restore. Assuming that the desired connection was completed to one of the repeaters respectively terminating the trunk lines 44 and 44', the restoration of the relay R1530 is effective to open the loop circuit extending to the operated repeater, whereby the operated relay R1520 is deenergized and restores. Thus, all of the relay equipment embodied in the trunk selecting apparatus of Fig. 15 is restored to normal, and this apparatus is conditioned for further use. In this regard, it is pointed out that, when the hold relay R1510 restores, it opens, at RA1514, a point in the above-described path for impressing ground potential upon the two control conductors C1376 and C1461, whereby the repeater of Fig. 14 is marked as idle in the bank contacts of the connector switches having access thereto. When the loop circuit extending to an operated one of the repeaters respectively terminating the trunk lines 44 and 44' is interrupted in response to the restoration of R1530, this operated repeater is released and, during its release, operates to transmit, in the manner previously explained, a supervisory pulse of alternating current to the operator's position in the exchange A, whereby the supervisory lamp provided at this position is energized to signal the operator that the connection is ready for release.

30 SECTION 12.—FORCED RELEASE OF THE ALTERNATING CURRENT REPEATERS

As previously pointed out, each of the alternating current repeaters 16, 24, 50, 51, 66, 72, etc., embodied in the system is arranged to be forcibly released in the event a current seizing pulse is transmitted thereto and no further pulses, corresponding to impulses dialed at a calling telephone station, are thereafter transmitted thereto within a predetermined time interval. This arrangement is for the purpose of preventing the repeaters from inadvertently being held in an operated condition when the seizure thereof results, not from calls routed thereto, but from electrical disturbances created on the respective associated trunk lines. For example, if an electrical transient of a periodic character is from natural causes created upon the trunk line 37 interconnecting the two repeaters 24 and 50, these two repeaters are both seized in the manner previously described with reference to the alternating current seizing pulses transmitted between the two indicated repeaters in the respective two directions. Briefly to summarize, when the transient voltage appears between the conductors of the trunk line 37, the alternating current relay R2650 embodied in the repeater 50 operates to complete, at RA2652, the previously traced circuit for energizing the upper winding of the relay R2710. The relay R2710 now partially operates to complete the previously traced path for short-circuiting its lower windings. When the transient voltage impressed between the conductors of the trunk line 37 dies out, the relay R2650 restores to open a point in the path short-circuiting the lower winding of R2710, permitting the two windings of this relay to be energized in series. The relay R2710 now fully operates to complete, at RA2711, RA2715 and RA2719, a loop circuit extending by way of the trunk line 61 to the incoming connector switch 53, whereby this incoming connector switch is seized and conditioned, in the manner previously explained, to respond to impulses transmitted thereto from the repeater 50. At

RA2717, the relay R2710 completes the previously-traced circuit for energizing the upper winding of the electropolarized relay R2710 in parallel with the lower winding of the relay R2640. At RA2718, the relay R2710 completes the previously-traced operating circuit for the slow-to-release relay R2605. The relay R2640, upon operating, initiates the cyclic operation of the three relays R2655, R2660 and R2670 and prepares the circuit for energizing the operating magnet 2787 of the stepping switch 2785, all in the manner pointed out previously. During each cycle of operation of the three enumerated relays, the circuit for energizing the magnet 2787 is completed with the result that the wiper 2786 is operated from its home position step by step over the contacts of the associated contact field. When this wiper is stepped to its first off-normal position, the off-normal springs 2789 are closed to prepare the circuit for energizing the release magnet 2788. The stepping operation of the switch 2785 continues until the wiper 2786 is operated to its ninth off-normal position, at which time an obvious circuit is completed for energizing the winding of the slow-to-release relay R2720. This relay, upon operating, opens, at RA2722 and RC2723, the holding circuit for the relay R2710 and completes, at RA2721 and RA2722, an alternative holding circuit for the indicated relay R2710, which alternative circuit extends by way of the grounded wiper 2786. Thereafter and when the wiper 2786 is stepped to its tenth off-normal position, the alternative holding circuit for the relay R2710 and the operating circuit for the relay R2701 are interrupted, causing these two relays to restore in the order named. Upon restoring, the relay R2710 opens, at RA2711, RA2715 and RA2719, three points in the established loop circuit extending to the incoming connector switch 53, whereby the relay equipment embodied in this incoming connector switch is restored to normal and the switch is conditioned for further use. At RA2718, the relay R2710 opens the previously traced operating circuit for the relay R2605, causing the last-mentioned relay to restore. At RA2717, the relay R2710 interrupts the above-mentioned circuit for energizing the upper winding of R2700 and the lower winding of R2640 in parallel. Thereafter, and during the portion of the next cycle of operation of the three relays R2655, R2660 and R2670 when the last two thereof are restored, the previously traced holding circuit for the relay R2640 is interrupted and this relay restores to arrest the cyclic operation of the three enumerated relays and the operation of the stepping switch 2785. Also, upon restoring, the relay R2640 completes, at RA2641 and its associated resting contact, the previously traced circuit for energizing the release magnet 2788 with the result that the wiper 2786 is returned to its home position and the off-normal springs 2789 are opened. Following the release of the stepping switch 2785, the repeater 50 is fully restored to normal and is conditioned for further use.

The manner in which the repeater 24 terminating the opposite end of the trunk line 37 in the exchange B responds to the transient voltage impressed between the conductors of the trunk line 37 and is thereafter forcibly released is identical with the operation of the repeater 50 as just described.

While there has been described what is at present considered to be the preferred embodiment of the invention, it will be understood that various modifications may be made therein, and it is intended to cover in the appended claims all such modifications as fall within the true spirit and scope of the invention.

What is claimed is:

1. In a telephone system, a first repeater, a second repeater including a stepping switch having a normal position and operative to a plurality of off-normal positions, said repeaters being connected in tandem in the order named; means operative to seize said first repeater, a trunk line extending to said second repeater, means included in said first repeater and operative in response to the seizure of said first repeater for transmitting a seizing pulse of alternating current to said second repeater, means included in said second repeater and responsive to said alternating current seizing pulse for initiating the operation of said stepping switch, means included in said first repeater and responsive to direct current impulses transmitted to said first repeater for transmitting corresponding pulses of alternating current to said second repeater, means included in said second repeater and responsive to said alternating current pulses for transmitting corresponding direct current impulses over said trunk line and for arresting the operation of said stepping switch, and means controlled by said stepping switch for releasing said second repeater in the event at least one pulse of alternating current, following said alternating current seizing pulse, is not transmitted to said second repeater before said stepping switch is operated to a predetermined off-normal position.
2. In a telephone system, a plurality of telephone stations; a first repeater, a second repeater and an automatic switch adapted to be connected in tandem in the order named in establishing a connection between two of said telephone stations; said first repeater including a first stepping switch and said second repeater including a second stepping switch, each of said stepping switches having a normal position and being operative to a plurality of off-normal positions, means included in said first repeater and operative when a connection is routed thereto from a calling one of said telephone stations for transmitting a seizing pulse of alternating current to said second repeater, means included in said second repeater and responsive to said alternating current seizing pulse for initiating the operation of said second stepping switch, means included in said first repeater and responsive to direct current impulses transmitted thereto for transmitting corresponding pulses of alternating current to said second repeater, means included in said second repeater and responsive to said alternating current pulses for arresting the operation of said second stepping switch and for transmitting corresponding direct current impulses to said automatic switch, whereby said automatic switch is caused to route the connection to a called one of said telephone stations, means controlled by said second stepping switch for releasing said second repeater in the event at least one pulse of alternating current, following said alternating current seizing pulse, is not transmitted to said second repeater before said second stepping switch is operated to a first predetermined off-normal position, means included in said first repeater and operative in response to the release of said connection at said calling telephone station for initiating the operation of said first stepping switch and for causing a release

pulse of alternating current to be transmitted to said second repeater, means operative in response to the operation of said first stepping switch to a predetermined off-normal position for terminating said alternating current release pulse and for releasing said first repeater, means included in said second repeater and responsive to said alternating current release pulse for again initiating the operation of said second stepping switch, and means operative in response to the last-mentioned operation of said second stepping switch to a second predetermined off-normal position for causing said second repeater to be released.

3. In a telephone system, a plurality of telephone stations; a first repeater, a second repeater and an automatic switch adapted to be connected in tandem in the order named in establishing a connection between two of said telephone stations; said first repeater including a battery reversing relay having two operating positions and a first stepping switch, said second repeater including a second stepping switch, each of said stepping switches having a normal position and being operative to a plurality of off-normal positions, means included in said first repeater and operative when a connection is routed thereto from a calling one of said telephone stations for transmitting a seizing pulse of alternating current to said second repeater, means included in said second repeater and responsive to said alternating current seizing pulse for initiating the operation of the second stepping switch, means included in said first repeater and responsive to direct current impulses transmitted thereto for transmitting corresponding pulses of alternating current to said second repeater, means included in said second repeater and responsive to said alternating current pulses for arresting the operation of said second stepping switch and for transmitting corresponding direct current impulses to said automatic switch, whereby said automatic switch is caused to route the connection to a called one of said telephone stations, means included in said second repeater and operative when the call is answered at said called telephone station for causing a supervisory pulse of alternating current to be transmitted to said first repeater, means included in said first repeater and responsive to said alternating current supervisory pulse for causing said battery reversing relay to operate to one of its two operating positions, means controlled by said second stepping switch for releasing said second repeater in the event at least one pulse of alternating current, following said alternating current seizing pulse, is not transmitted to said second repeater before said second stepping switch is operated to a first predetermined off-normal position, means included in said second repeater and operative when the connection is released at said called telephone station for causing a second supervisory pulse of alternating current to be transmitted to said first repeater, means included in said first repeater and responsive to said second alternating current supervisory pulse for causing said battery reversing relay to operate to the other of its two operating positions, means included in said first repeater and operative in response to the release of said connection at said calling telephone station for initiating the operation of said first stepping switch and for causing a release pulse of alternating current to be transmitted to said second repeater, means operative in response to the operation of said first stepping switch to a predetermined off-normal

position for terminating said alternating current release pulse and for releasing said first repeater, means included in said second repeater and responsive to said alternating current release pulse for again initiating the operation of said second stepping switch, and means operative in response to the last-mentioned operation of said second stepping switch to a second predetermined off-normal position for causing said second repeater to be released.

4. In a telephone system, a plurality of telephone stations; a first repeater, a second repeater and an automatic switch adapted to be connected in tandem in the order named in establishing a connection between two of said telephone stations; said first repeater including a first stepping switch and said second repeater including a second stepping switch, each of said stepping switches having a normal position and being operative to a plurality of off-normal positions, means included in said first repeater and operative when a connection is routed thereto from a calling one of said telephone stations for transmitting a seizing pulse of alternating current to said second repeater, means included in said second repeater and responsive to said alternating current seizing pulse for initiating the operation of said second stepping switch, means included in said first repeater and responsive to direct current impulses transmitted thereto from the calling telephone station for transmitting corresponding pulses of alternating current to said second repeater, means included in said second repeater and responsive to the first of said alternating current pulses for arresting the operation of said second stepping switch, means included in said second repeater and responsive to said alternating current pulses for transmitting corresponding direct current impulses to said automatic switch, whereby said automatic switch is caused to route the connection to a called one of said telephone stations, means included in said first repeater and operative in response to the release of said connection at said calling telephone station for initiating the operation of said first stepping switch and for causing a release pulse of alternating current to be transmitted to said second repeater, means operative in response to the operation of said first stepping switch to a predetermined off-normal position for terminating said alternating current release pulse and for releasing said first repeater, means included in said second repeater and responsive to said alternating current release pulse for again initiating the operation of said second stepping switch, and means operative in response to the last-mentioned operation of said second stepping switch to a second predetermined off-normal position for releasing said second repeater.

5. In a telephone system, a plurality of telephone stations; a first repeater, a second repeater and an automatic switch adapted to be connected in tandem in the order named in establishing a connection between two of said telephone stations; said first repeater including a battery reversing relay having two operating positions and a first stepping switch, said second repeater including a second stepping switch, each of said stepping switches having a normal position and being operative to a plurality of off-normal positions, means included in said first repeater and operative when a connection is routed thereto from a calling one of said telephone stations for transmitting a seizing pulse of alter-

- nating current to said second repeater, means included in said second repeater and responsive to said alternating current seizing pulse for initiating the operation of said second stepping switch, means included in said first repeater and responsive to direct current impulses transmitted thereto from the calling telephone station for transmitting corresponding pulses of alternating current to said second repeater, means included in said second repeater and responsive to the first of said alternating current pulses for arresting the operation of said second stepping switch, means included in said second repeater and responsive to said alternating current pulses for transmitting corresponding direct current impulses to said automatic switch, whereby said automatic switch is caused to route the connection to a called one of said telephone stations, means included in said first repeater and operative when the call is answered at said called substation for causing a supervisory pulse of alternating current to be transmitted to said first repeater, means included in said first repeater and responsive to said alternating current supervisory pulse for causing said battery reversing relay to operate to one of its two operating positions, means included in said second repeater and operative when the connection is released at said called telephone station for causing a second supervisory pulse of alternating current to be transmitted to said first repeater, means included in said first repeater and responsive to said second alternating current supervisory pulse for causing said battery reversing relay to operate to the other of its two operating positions, means included in said first repeater and operative in response to the release of said connection at said calling telephone station for initiating the operation of said first stepping switch and for causing a release pulse of alternating current to be transmitted to said second repeater, means operative in response to the operation of said first stepping switch to a predetermined off-normal position for terminating said alternating current release pulse and for releasing said first repeater, means included in said second repeater and responsive to said alternating current release pulse for again initiating the operation of said second stepping switch, and means operative in response to the last-mentioned operation of said second stepping switch to a second predetermined off-normal position for releasing said second repeater.
6. In a telephone system, a plurality of telephone stations; a first repeater, a second repeater and an automatic switch adapted to be connected in tandem in the order named in establishing a connection between two of said telephone stations; said first repeater including a battery reversing relay having two operating positions and a first stepping switch, said second repeater including a second stepping switch, each of said stepping switches having a normal position and being operative to a plurality of off-normal positions, means included in said first repeater and operative when a connection is routed thereto from a calling one of said telephone stations for transmitting a seizing pulse of alternating current to said second repeater, means included in said second repeater and responsive to said alternating current seizing pulse for initiating the operation of said second stepping switch, means included in said first repeater and responsive to direct current impulses transmitted thereto from the calling telephone station for transmitting corresponding pulses of alternating current to said second repeater, means included in said second repeater and responsive to the first of said alternating current pulses for arresting the operation of said second stepping switch, means included in said second repeater and responsive to said alternating current pulses for transmitting corresponding direct current impulses to said automatic switch, whereby said automatic switch is caused to route the connection to a called one of said telephone stations, means included in said first repeater and operative when the call is answered at said called telephone station for causing a supervisory pulse of alternating current to be transmitted to said first repeater, means included in said first repeater and responsive to said alternating current supervisory pulse for causing said battery reversing relay to operate from one of its two operating positions to the other, and means controlled by said second stepping switch for releasing said second repeater in the event at least one pulse of alternating current, following said alternating current seizing pulse, is not transmitted to said second repeater before said second stepping switch is operated to a predetermined off-normal position.
7. In a telephone system, a plurality of telephone stations; a first repeater, a second repeater and an automatic switch adapted to be connected in tandem in the order named in establishing a connection between two of said telephone stations; said first repeater including a battery reversing relay having two operating positions and a first stepping switch, said second repeater including a second stepping switch, each of said stepping switches having a normal position and being operative to a plurality of off-normal positions, means included in said first repeater and operative when a connection is routed thereto from a calling one of said telephone stations for transmitting a seizing pulse of alternating current to said second repeater, means included in said second repeater and responsive to said alternating current seizing pulse for initiating the operation of said second stepping switch, means included in said first repeater and responsive to direct current impulses transmitted thereto from the calling telephone station for transmitting corresponding pulses of alternating current to said second repeater, means included in said second repeater and responsive to the first of said alternating current pulses for arresting the operation of said second stepping switch, means included in said second repeater and responsive to said alternating current pulses for transmitting corresponding direct current impulses to said automatic switch, whereby said automatic switch is caused to route the connection to a called one of said telephone stations, means included in said first repeater and operative when the call is answered at said called telephone station for causing a supervisory pulse of alternating current to be transmitted to said first repeater, means included in said first repeater and responsive to said alternating current supervisory pulse for causing said battery reversing relay to operate from one of its two operating positions to the other, means controlled by said second stepping switch for releasing said second repeater in the event at least one pulse of alternating current, following said alternating current seizing pulse, is not transmitted to said second repeater before said second stepping switch is operated to a predetermined off-normal position, means op-

erative when the connection is released at said calling telephone station for initiating the operation of said stepping switches, and means controlled by said stepping switches for releasing said repeaters.

8. In a telephone system, a plurality of telephone stations, a first repeater including a first stepping switch, a second repeater including a second stepping switch, a trunk line extending to said second repeater, said repeaters and said trunk line being adapted to be connected in tandem in the order named in establishing a connection between two of said telephone stations, means included in said first repeater and operative when the connection is extended to said repeater for transmitting a seizing pulse of alternating current to said second repeater, means included in said second repeater and responsive to said alternating current seizing pulse for initiating the operation of said second stepping switch, means included in said first repeater and responsive to direct current impulses transmitted thereto for transmitting corresponding pulses of alternating current to said second repeater, means included in said second repeater and responsive to said alternating current pulses for transmitting corresponding direct current impulses over said trunk line and for arresting the operation of said second switch, means controlled by said second stepping switch for releasing said second repeater in the event at least one pulse of alternating current, following said alternating current seizing pulse, is not transmitted thereto before said second stepping switch is operated to a predetermined off-normal position, means operative when the connection is released at one end thereof for initiating the operation of said stepping switches, and means controlled by said stepping switches for releasing said repeaters.

9. In a telephone system, a plurality of telephone stations, a pair of repeaters each including a stepping switch, said repeaters being adapted to be connected in tandem in establishing a connection between two of said telephone stations, means operative when the connection is released at one end thereof for initiating the operation of said stepping switches, and means controlled by said stepping switches for releasing said repeaters.

10. In a telephone system, a plurality of telephone stations, a first repeater including a first stepping switch, a second repeater including a second stepping switch, each of said stepping switches having a normal position and a plurality of corresponding off-normal positions, said repeaters being adapted to be connected in tandem in the order named in establishing a connection between two of said telephone stations, means operative when the connection is released at the calling end thereof for initiating the operation of said stepping switches, means operative in response to the operation of said second stepping switch to one off-normal position for conditioning said second repeater to be released, and means operative when said first stepping switch is thereafter operated to a second off-normal position, succeeding said one off-normal position, for releasing said second repeater.

11. In a telephone system, a plurality of telephone stations, a first repeater including a first stepping switch, a second repeater including a second stepping switch, each of said stepping switches having a normal position and a plurality of corresponding off-normal positions, said repeaters being adapted to be connected in tan- 70

dem in the order named in establishing a connection between two of said telephone stations, means operative when the connection is released at the calling end thereof for initiating the operation of said stepping switches, means operative in response to the operation of said second stepping switch to one off-normal position for conditioning said second repeater to be released, means included in said second repeater and operative in response to the operation of said first stepping switch to a second off-normal position, succeeding said one off-normal position, for releasing said second repeater, and means included in said first repeater and also responsive to the operation of said first stepping switch to said second off-normal position for releasing said first repeater.

12. In a telephone system, a plurality of telephone stations, a first repeater including a first stepping switch, a second repeater including a second stepping switch, each of said stepping switches having a normal position and a plurality of corresponding off-normal positions, said repeaters being adapted to be connected in tandem in the order named in establishing a connection between two of said telephone stations, means included in said first repeater and operative when the connection is released at the calling end thereof for causing an alternating current pulse to be transmitted to said second repeater and for initiating the operation of said first stepping switch, means included in said second repeater and responsive to said alternating current pulse for initiating the operation of said second stepping switch, means included in said second repeater and operative in response to the operation of said second stepping switch to one off-normal position for conditioning said second repeater to be released, means included in said first repeater and operative in response to the operation of said first stepping switch to a second off-normal position, succeeding said one off-normal position, for terminating said alternating current pulse, and means included in said second repeater and operative when said alternating current pulse is terminated for releasing said second repeater.

13. In a telephone system, a plurality of telephone stations, a first repeater including a first stepping switch, a second repeater including a second stepping switch, each of said stepping switches having a normal position and a plurality of corresponding off-normal positions, said repeaters being adapted to be connected in tandem in the order named in establishing a connection between two of said telephone stations, means included in said first repeater and operative when the connection is released at the calling end thereof for causing an alternating current pulse to be transmitted to said second repeater and for initiating the operation of said first stepping switch, means included in said second repeater and responsive to said alternating current pulse for initiating the operation of said second stepping switch, means included in said second repeater and operative in response to the operation of said second stepping switch to one off-normal position for conditioning said second repeater to be released, means included in said first repeater and operative in response to the operation of said first stepping switch to a second off-normal position, succeeding said one off-normal position, for terminating said alternating current pulse, means included in said second repeater and operative when said alternating current pulse is terminated for releasing said sec-

ond repeater, and means included in said first repeater and also operative in response to the operation of said first switch to said second off-normal position for releasing said first repeater.

14. In a telephone system a plurality of telephone stations, a first repeater having a pair of incoming trunk lines extending thereto, said first repeater including a first stepping switch and a battery reversing relay having two operating positions, a second repeater including a second stepping switch, each of said stepping switches including a normal position and being operative to a plurality of off-normal positions, an automatic switch; one of said trunk lines, said first repeater, said second repeater and said automatic switch being adapted to be connected in tandem in the order named in establishing a connection between two of said telephone stations, means included in said first repeater and operative when a connection is routed thereto from a calling one of said telephone stations for transmitting a seizing pulse of alternating current to said second repeater, means included in said second repeater and responsive to said alternating current seizing pulse for initiating the operation of said second stepping switch, means included in said first repeater and responsive to direct current impulses transmitted thereto from said calling telephone station for transmitting corresponding alternating current pulses to said second repeater, means included in said second repeater and responsive to said alternating current pulses for arresting the operation of said second stepping switch and for transmitting corresponding direct current impulses to said automatic switch, whereby said automatic switch is caused to route the connection to a called one of said telephone stations, means included in said second repeater and operative when the call is answered at the called telephone station for causing a supervisory pulse of alternating current to be transmitted to said first repeater, means included in said first repeater and responsive to said alternating current supervisory pulse for causing said battery reversing relay to operate to one of its two operating positions, said trunk lines and said battery reversing relay being so connected and arranged that operation of said battery reversing relay is effective to reverse the polarity of the voltage impressed upon only one of said trunk lines, means included in said first repeater and operative when the connection is released at said called telephone station for causing a second supervisory pulse of alternating current to be transmitted to said first repeater, means included in said first repeater and responsive to said second alternating current supervisory pulse for causing said battery reversing relay to operate to the other of its two operating positions, means included in said first repeater and operative in response to the release of the connection at said calling telephone station for initiating the operation of said first stepping switch and for causing a release pulse of alternating current to be transmitted to said second repeater, means operative in response to the operation of said first stepping switch to a predetermined off-normal position for terminating said alternating current release pulse and for releasing said first repeater, means included in said second repeater and responsive to said alternating current release pulse for again initiating the operation of said second stepping switch, and means operative in response to the last-mentioned operation of said second stepping switch to a second predetermined off-normal po-

75 sition for causing said second repeater to be released.

15. An impulse repeater adapted for use in a telephone system and having a trunk line extending thereto, said repeater comprising, in combination, a stepping switch having a normal position and operative to a plurality of off-normal positions, means responsive to a seizing pulse of alternating current transmitted over said trunk line for initiating the operation of said switch and for conditioning said repeater to respond to pulses of alternating current transmitted by way of said trunk line, means controlled by said switch for releasing said repeater in the event at least one additional alternating current pulse, succeeding said alternating current seizing pulse, is not transmitted over said trunk line to said repeater before said switch is operated to a predetermined off-normal position, and means responsive to an additional pulse of alternating current transmitted over said trunk line for arresting the operation of said switch.

16. An impulse repeater adapted for use in a telephone system and having a trunk line extending thereto, said repeater comprising, in combination, a stepping switch including an operating magnet, said switch having a normal position and being operative to a plurality of off-normal positions, an operating circuit for said magnet, a plurality of cyclically operating relays, means responsive to a seizing pulse of alternating current transmitted over said trunk line for preparing said operating circuit and for initiating the cyclic operation of said relays, said relays being connected and arranged to complete said operating circuit during each cycle of operation thereof, means controlled by said switch for releasing said repeater in the event at least one additional alternating current pulse, succeeding said alternating current seizing pulse, is not transmitted over said trunk line to said repeater before said switch is operated to a predetermined off-normal position, and means responsive to an additional pulse of alternating current transmitted over said trunk line for arresting the operation of said relays, thereby to arrest the operation of said switch.

17. An impulse repeater adapted for use in a telephone system and having a trunk line extending thereto, said repeater comprising, in combination, a stepping switch including an operating magnet, said switch having a normal position and being operative to a plurality of off-normal positions, an operating circuit for said magnet, a plurality of cyclically operating relays, an alternating current relay connected to be energized by an alternating current seizing pulse transmitted over said trunk line to said repeater, a two-step relay having operating and holding circuits so connected and arranged that said two-step relay partially operates in response to the operation of said alternating current relay and completes its operation in response to the restoration of said alternating current relay at the end of said seizing pulse, means responsive to the complete operation of said two-step relay for initiating the cyclic operation of said first-mentioned relays and for preparing the operating circuit for said operating magnet, said cyclically operating relays being connected and arranged to complete the operating circuit for said magnet during each cycle of operation thereof, whereby operation of said switch is initiated, means controlled by said switch for interrupting the holding circuit for said two-step

relay, thereby to release said repeater, in the event at least one additional alternating current pulse, succeeding said alternating current seizing pulse, is not transmitted over said trunk line to said repeater before said switch is operated to a predetermined off-normal position, and means responsive to an additional pulse of alternating current transmitted over said trunk line to said repeater for arresting the operation of said cyclically operating relays, thereby to arrest the operation of said switch.

18. An impulse repeater adapted for use in a telephone system and having a trunk line extending thereto, said repeater comprising, in combination, a stepping switch including an operating magnet, said switch having a normal position and being operative to a plurality of off-normal positions, an operating circuit for said magnet, a plurality of cyclically operating relays, a control relay operative to prepare said operating circuit and to initiate the cyclic operation of said relays, an operating circuit for said control relay, an alternating current relay connected to be energized by an alternating current seizing pulse transmitted over said trunk line to said repeater, a two-step relay having operating and holding circuits so connected and arranged that said two-step relay partially operates in response to the operation of said alternating current relay and completes its operation in response to the restoration of said alternating current relay at the end of said seizing pulse, means responsive to the complete operation of said two-step relay for conditioning said repeater to respond to alternating current pulses transmitted thereto over said trunk line and for completing the operating circuit for said control relay, said cyclically operating relays being connected and arranged to complete the operating circuit for said magnet during each cycle of operation thereof, whereby operation of said switch is initiated, means controlled by said switch for interrupting the holding circuit for said two-step relay, thereby to release said repeater, in the event at least one additional alternating current pulse, succeeding said alternating current seizing pulse, is not transmitted over said trunk line to said repeater before said switch is operated to a predetermined off-normal position, and means responsive to an additional pulse of alternating current transmitted over said trunk line to said repeater for interrupting the operating circuit for said control relay, thereby to arrest the operation of said switch and said cyclically operating relays.

19. An impulse repeater adapted for use in a telephone system and having a trunk line extending thereto, said repeater comprising, in combination, a stepping switch having a normal position and operative to a plurality of off-normal positions, means responsive to a seizing pulse of alternating current transmitted over said trunk line for initiating the operation of said switch and for conditioning said repeater to respond to pulses of alternating current transmitted by way of said trunk line, means controlled by said switch for releasing said repeater in the event at least one additional alternating current pulse, succeeding said alternating current seizing pulse, is not transmitted over said trunk line to said repeater before said switch is operated to a predetermined off-normal position, means responsive to an additional pulse of alternating current transmitted over said trunk line for arresting the operation of said switch, 75

means responsive to a release pulse of alternating current transmitted over said trunk line to said repeater for again initiating the operation of said switch, and means operative in response to the operation of said switch to a second off-normal position for causing said repeater to be released.

20. An impulse repeater adapted for use in a telephone system and having a trunk line extending thereto, said repeater comprising, in combination, a stepping switch having a normal position and operative to a plurality of off-normal positions, means responsive to a seizing pulse of alternating current transmitted over said trunk line for initiating the operation of said switch and for conditioning said repeater to respond to pulses of alternating current transmitted by way of said trunk line, means controlled by said switch for releasing said repeater in the event at least one additional alternating current pulse, succeeding said alternating current seizing pulse, is not transmitted over said trunk line to said repeater before said switch is operated to a predetermined off-normal position, means responsive to an additional pulse of alternating current transmitted over said trunk line for arresting the operation of said switch and for causing said switch to be returned to its normal position, means responsive to a release pulse of alternating current transmitted over said trunk line to said repeater for again initiating the operation of said switch, means operative in response to the last-mentioned operation of said switch to a second off-normal position, preceding said predetermined off-normal position, for conditioning said repeater to be released, and means operative in response to the termination of said alternating current release pulse for releasing said repeater.

21. An impulse repeater adapted for use in a telephone system and having a trunk line extending thereto, said repeater comprising, in combination, a stepping switch including an operating magnet, said switch having a normal position and being operative to a plurality of off-normal positions, an operating circuit for said magnet, a plurality of cyclically operating relays, means responsive to a seizing pulse of alternating current transmitted over said trunk line for preparing said operating circuit and for initiating the cyclic operation of said relays, said relays being connected and arranged to complete said operating circuit during each cycle of operation thereof, means controlled by said switch for releasing said repeater in the event at least one additional alternating current pulse, succeeding said alternating current seizing pulse, is not transmitted over said trunk line to said repeater before said switch is operated to a predetermined off-normal position, means responsive to an additional pulse of alternating current transmitted over said trunk line for arresting the operation of said relays, thereby to arrest the operation of said switch, means responsive to a release pulse of alternating current transmitted over said trunk line to said repeater for preparing said operating circuit and for again initiating the operation of said relays, thereby to initiate the operation of said switch, and means operative in response to the last-mentioned operation of said switch to a second off-normal position for causing said repeater to be released.

22. An impulse repeater adapted for use in a telephone system and having a trunk line extending thereto, said repeater comprising, in combi-

nation, a stepping switch including an operating magnet, said switch having a normal position and being operative to a plurality of off-normal positions, an operating circuit for said magnet, a plurality of cyclically operating relays, means responsive to a seizing pulse of alternating current transmitted over said trunk line for preparing said operating circuit and for initiating the cyclic operation of said relays, said relays being connected and arranged to complete said operating circuit during each cycle of operation thereof, means controlled by said switch for releasing said repeater in the event at least one additional alternating current pulse, succeeding said alternating current seizing pulse, is not transmitted over said trunk line to said repeater before said switch is operated to a predetermined off-normal position, means responsive to an additional pulse of alternating current transmitted over said trunk line for arresting the operation of said relays, thereby to arrest the operation of said switch and for causing said switch to be returned to its normal position, means responsive to a release pulse of alternating current transmitted over said trunk line to said repeater for preparing said operating circuit and for again initiating the operation of said relays, thereby to initiate the operation of said switch, means operative in response to the last-mentioned operation of said switch to a second off-normal position, preceding said predetermined off-normal position, for conditioning said repeater to be released, and means operative in response to the termination of said alternating current release pulse for releasing said repeater.

23. An impulse repeater adapted for use in a telephone system and having a trunk line extending thereto, said repeater comprising, in combination, a stepping switch including an operating magnet, said switch having a normal position and being operative to a plurality of off-normal positions, an operating circuit for said magnet, a plurality of cyclically operating relays, an alternating current relay connected to be energized by an alternating current seizing pulse transmitted over said trunk line to said repeater, a two-step relay having operating and holding circuits so connected and arranged that said two-step relay partially operates in response to the operation of said alternating current relay and completes its operation in response to the restoration of said alternating current relay at the end of said seizing pulse, means responsive to the complete operation of said two-step relay for initiating the cyclic operation of said first-mentioned relays and for preparing the operating circuit for said operating magnet, said cyclically operating relays being connected and arranged to complete the operating circuit for said magnet during each cycle of operation thereof, whereby operation of said switch is initiated, means controlled by said switch for interrupting the holding circuit for said two-step relay, thereby to release said repeater, in the event at least one additional alternating current pulse, succeeding said alternating current seizing pulse, is not transmitted over said trunk line to said repeater before said switch is operated to a predetermined off-normal position, means responsive to an additional pulse of alternating current transmitted over said trunk line to said repeater for arresting the operation of said cyclically operating relays, thereby to arrest the operation of said switch, means responsive to the operation of said alternating current relay re-

5 sulting from a release pulse of alternating current transmitted over said trunk line to said repeater for again initiating the operation of said cyclically operating relays and for preparing the operating circuit for said magnet, whereby operation of said switch is again initiated, and means controlled jointly by said switch and said alternating current relay and operative in response to the operation of said switch to a second off-normal position for interrupting the holding circuit for said two-step relay, thereby to cause said repeater to be released.

10 24. An impulse repeater adapted for use in a telephone system and having a trunk line extending thereto, said repeater comprising, in combination, a stepping switch including an operating magnet, said switch having a normal position and being operative to a plurality of off-normal positions, an operating circuit for said magnet, a plurality of cyclically operating relays, an alternating current relay connected to be energized by an alternating current seizing pulse transmitted over said trunk line to said repeater, a two-step relay having operating and holding circuits so connected and arranged that said two-step relay partially operates in response to the operation of said alternating current relay and completes its operation in response to the restoration of said alternating current relay at the end of said seizing pulse, means responsive to the complete operation of said two-step relay for initiating the cyclic operation of said first-mentioned relays and for preparing the operating circuit for said operating magnet, said cyclically operating relays being connected and arranged to complete the operating circuit for said magnet during each cycle of operation thereof, whereby operation of said switch is initiated, means controlled by said switch for interrupting the holding circuit for said two-step relay, thereby to release said repeater, in the event at least one additional alternating current pulse, succeeding said alternating current seizing pulse, is not transmitted over said trunk line to said repeater before said switch is operated to a predetermined off-normal position, means responsive to an additional pulse of alternating current transmitted over said trunk line to said repeater for arresting the operation of said cyclically operating relays and for causing said switch to be returned to its normal position, means responsive to the operation of said alternating current relay resulting from a release pulse of alternating current transmitted over said trunk line to said repeater for again initiating the operation of said cyclically operating relays and for preparing the operating circuit for said magnet, whereby operation of said switch is again initiated, and means controlled jointly by said switch and said alternating current relay and operative in response to the operation of said switch to a second off-normal position, preceding said predetermined off-normal position, for interrupting the holding circuit for said two-step relay, thereby to cause said repeater to be released.

15 25. In a telephone system, a plurality of telephone stations, a repeater and a trunk line extending to said repeater, said repeater being adapted to be connected in tandem with said trunk line in establishing a connection between two of said telephone stations and comprising, in combination, a stepping switch including an operating magnet, said switch having a normal position and being operative to a plurality of off-normal positions, an operating circuit for said

magnet, a plurality of cyclically operating relays, means responsive to a seizing pulse of alternating current transmitted over said trunk line for preparing said operating circuit and for initiating the operation of said relays, said relays being connected and arranged to complete said operating circuit during each cycle of operation thereof, whereby operation of said last-named means is effective to initiate the operation of said switch, means controlled by said switch for releasing said repeater in the event at least one additional pulse of alternating current, succeeding said alternating current release pulse, is not transmitted over said trunk line to said repeater before said switch is operated to a predetermined off-normal position, means responsive to an additional pulse of alternating current transmitted over said trunk line to said repeater for arresting the operation of said relays, thereby to arrest the operation of said switch, means operative when the call routed through said repeater to a called telephone station is answered at the called telephone station for again initiating the operation of said relays and for causing a supervisory pulse of alternating current to be transmitted over said trunk line, and means responsive to the operation of said relays through one cycle of operation for controlling the length of said supervisory pulse of alternating current and for arresting the operation of said relays.

26. In a telephone system, a plurality of telephone stations, a repeater and a trunk line extending to said repeater, said repeater being adapted to be connected in tandem with said trunk line in establishing a connection between two of said telephone stations and comprising, in combination; a stepping switch including an operating magnet, said switch having a normal position and being operative to a plurality of off-normal positions, an operating circuit for said magnet, a plurality of cyclically operating relays, means responsive to a seizing pulse of alternating current transmitted over said trunk line for preparing said operating circuit and for initiating the operation of said relays, said relays being connected and arranged to complete said operating circuit during each cycle of operation thereof, whereby operation of said last-named means is effective to initiate the operation of said switch, means controlled by said switch for releasing said repeater in the event at least one additional pulse of alternating current, succeeding said alternating current release pulse, is not transmitted over said trunk line to said repeater before said switch is operated to a predetermined off-normal position, means responsive to an additional pulse of alternating current transmitted over said trunk line to said repeater for arresting the operation of said relays, thereby to arrest the operation of said switch, means operative when the call routed through said repeater to a called telephone station is answered at the called telephone station for again initiating the operation of said relays and for causing a supervisory pulse of alternating currents to be transmitted over said trunk line, and means responsive to the operation of said relays through one cycle of operation for controlling the length of said supervisory pulse of alternating current and for arresting the operation of said relays, said two last-named means and said relays being jointly operative, following the completion of said connection, to cause an additional supervisory pulse of alternating current to be transmitted over said trunk line each time said connection is broken

5 or recompleted at said called telephone station.

27. In a telephone system, a plurality of telephone stations, a repeater and a trunk line extending to said repeater, said repeater being adapted to be connected in tandem with said trunk line in establishing a connection between two of said telephone stations and comprising, in combination; a stepping switch including an operating magnet, said switch having a normal position and being operative to a plurality of off-normal positions, an operating circuit for said magnet, a plurality of cyclically operating relays, means responsive to a seizing pulse of alternating current transmitted over said trunk line for preparing said operating circuit and for initiating the operation of said relays, said relays being connected and arranged to complete said operating circuit during each cycle of operation thereof, whereby operation of said last-named means is effective to initiate the operation of said switch, means controlled by said switch for releasing said repeater in the event at least one additional pulse of alternating current, succeeding said alternating current release pulse, is not transmitted over said trunk line to said repeater before said switch is operated to a predetermined off-normal position, means responsive to an additional pulse of alternating current transmitted over said trunk line to said repeater for arresting the operation of said relays, thereby to arrest the operation of said switch, means operative when the call routed through said repeater to a called telephone station is answered at the called telephone station for again initiating the operation of said relays and for causing a supervisory pulse of alternating current to be transmitted over said trunk line, means responsive to the operation of said relays through one cycle of operation for controlling the length of said supervisory pulse of alternating current and for arresting the operation of said relays, means responsive to a release pulse of alternating current transmitted over said trunk line to said repeater for again initiating the operation of said relays and for preparing said operating circuit, thereby to initiate the operation of said switch, and means operative in response to the last-mentioned operation of said switch to a second off-normal position for causing said repeater to be released.

28. In a telephone system, a plurality of telephone stations, a repeater and a trunk line extending to said repeater, said repeater being adapted to be connected in tandem with said trunk line in establishing a connection between two of said telephone stations and comprising, in combination; a stepping switch including an operating magnet, said switch having a normal position and being operative to a plurality of off-normal positions, an operating circuit for said magnet, a plurality of cyclically operating relays, means responsive to a seizing pulse of alternating current transmitted over said trunk line for preparing said operating circuit and for initiating the operation of said relays, said relays being connected and arranged to complete said operating circuit during each cycle of operation thereof, whereby operation of said last-named means is effective to initiate the operation of said switch, means controlled by said switch for releasing said repeater in the event at least one additional pulse of alternating current, succeeding said alternating current release pulse, is not transmitted over said trunk line to said repeater before said switch is operated to a predetermined

off-normal position, means responsive to an additional pulse of alternating current transmitted over said trunk line to said repeater for arresting the operation of said relays, thereby to arrest the operation of said switch, means operative when the call routed through said repeater to a called telephone station is answered at the called telephone station for again initiating the operation of said relays and for causing a supervisory pulse of alternating current to be transmitted over said trunk line, means responsive to the operation of said relays through one cycle of operation for controlling the length of said supervisory pulse of alternating current and for arresting the operation of said relays, said two last-named means and said relays being jointly operative, following the completion of said connection, to cause an additional supervisory pulse of alternating current to be transmitted over said trunk line each time said connection is broken or recompleted at said called telephone station, means responsive to a release pulse of alternating current transmitted over said trunk line to said repeater for again initiating the operation of said relays and for preparing said operating circuit, thereby to initiate the operation of said switch, and means operative in response to the last-mentioned operation of said switch to a second off-normal position for causing said repeater to be released.

29. In a telephone system, a plurality of telephone stations, a repeater and a trunk line extending to said repeater, said repeater being adapted to be connected in tandem with said trunk line in establishing a connection between two of said telephone stations and comprising, in combination; a stepping switch including an operating magnet, said stepping switch having a normal position and being operative to a plurality of off-normal positions, an operating circuit for said magnet, a plurality of cyclically operative relays, an alternating current relay connected and arranged to be energized by an alternating current seizing pulse transmitted over said trunk line to said repeater, a two-step relay having operating and holding circuits so connected and arranged that said two-step relay partially operates in response to the operation of said alternating current relay and completes its operation in response to the restoration of said alternating current relay at the end of said seizing pulse, a control relay operative to prepare the operating circuit for said magnet and to initiate the operation of said cyclically operating relays in response to the complete operation of said two-step relay, said cyclically operating relays being connected and arranged to complete the operating circuit for said magnet during each cycle of operation thereof, whereby operation of said switch is initiated in response to operation of said control relay, means controlled by said switch for interrupting the holding circuit for said two-step relay, thereby to cause said repeater to be released, in the event at least one additional alternating current pulse, succeeding said alternating current seizing pulse, is not transmitted over said trunk line to said repeater before said switch is operated to a predetermined off-normal position, means responsive to an additional pulse of alternating current transmitted over said trunk line to said repeater for causing the restoration of said control relay, thereby to arrest the operation of said cyclically operating relays and said switch, means independent of said control relay and operative when the call

routed through said repeater to a called telephone station is answered at the called telephone station for again initiating the operation of said cyclically operating relays and for causing a supervisory pulse of alternating current to be transmitted from said repeater over said trunk line, and means responsive to the operation of said cyclically operating relays through one cycle of operation for controlling the length of said supervisory pulse of alternating current and for arresting the operation of said cyclically operating relays, said two last-named means and said cyclically operating relays being jointly operative following the completion of said connection to cause an additional supervisory pulse of alternating current to be transmitted over said trunk line each time said connection is broken or recompleted at said called telephone station.

30. In a telephone system, a plurality of telephone stations, a repeater and a trunk line extending to said repeater, said repeater being adapted to be connected in tandem with said trunk line in establishing a connection between two of said telephone stations and comprising, in combination; a stepping switch including an operating magnet, said stepping switch having a normal position and being operative to a plurality of off-normal positions, an operating circuit for said magnet, a plurality of cyclically operative relays, an alternating current relay connected and arranged to be energized by an alternating current seizing pulse transmitted over said trunk line to said repeater, a two-step relay having operating and holding circuits so connected and arranged that said two-step relay partially operates in response to the operation of said alternating current relay and completes its operation in response to the restoration of said alternating current relay at the end of said seizing pulse, a control relay operative to prepare the operating circuit for said magnet and to initiate the operation of said cyclically operating relays in response to the complete operation of said two-step relay, said cyclically operating relays being connected and arranged to complete the operating circuit for said magnet during each cycle of operation thereof, whereby operation of said switch is initiated in response to operation of said control relay, means controlled by said switch for interrupting the holding circuit for said two-step relay, thereby to cause said repeater to be released, in the event at least one additional alternating current pulse, succeeding said alternating current seizing pulse, is not transmitted over said trunk line to said repeater before said switch is operated to a predetermined off-normal position, means responsive to an additional pulse of alternating current transmitted over said trunk line to said repeater for causing the restoration of said control relay, thereby to arrest the operation of said cyclically operating relays and said switch, means independent of said control relay and operative when the call routed through said repeater to a called telephone station is answered at the called telephone station for again initiating the operation of said cyclically operating relays and for causing a supervisory pulse of alternating current to be transmitted from said repeater over said trunk line, and means responsive to the operation of said cyclically operating relays through one cycle of operation for controlling the length of said supervisory pulse of alternating current and for arresting the operation of said cyclically operating relays, said two last-named means and said cyclically operating relays being jointly operative following the completion of said connection to cause an additional supervisory pulse of alternating current to be transmitted over said trunk line each time said connection is broken or recompleted at said called telephone station.

31. In a telephone system, a plurality of tele-

phone stations, a repeater including a stepping switch having a normal position and operative to a plurality of off-normal positions, a first trunk line extending to said repeater, an automatic switch, a second trunk line extending between said repeater and said automatic switch and comprising a pair of line conductors; said first trunk line, said repeater, said second trunk line and said automatic switch being adapted to be connected in tandem in the order named in establishing a connection between two of said telephone stations; means included in said repeater and responsive to a seizing pulse of alternating current transmitted over said first trunk line to said repeater for initiating the operation of said stepping switch, means included in said repeater and responsive to relatively short alternating current pulses transmitted over said first trunk line to said repeater for arresting the operation of said stepping switch and for transmitting corresponding direct current impulses over said second trunk line to said automatic switch, whereby said automatic switch is caused to operate to select the called one of said telephone stations, a normally incomplete path for impressing a predetermined potential upon one of said line conductors, means included in said repeater and responsive to a relatively long supervisory pulse of alternating current transmitted over said first trunk line to said repeater for again initiating the operation of said stepping switch and for preparing a point in said path, means operative to complete said path for an interval following the end of said alternating current supervisory pulse and to arrest the last-mentioned operation of said stepping switch, means included in said automatic switch and responsive to the completion of said path for completing a talking connection to said called telephone station when said called telephone station is busy, means included in said repeater and responsive to a release pulse of alternating current of greater duration than said supervisory pulse and transmitted over said trunk line to said repeater for causing said stepping switch to operate to a predetermined off-normal position, and means operative in response to the operation of said stepping switch to said predetermined off-normal position for causing said repeater to be released.

32. In a telephone system, a plurality of telephone stations, a repeater including a stepping switch having a normal position and operative to a plurality of off-normal positions, a first trunk line extending to said repeater, an automatic switch, a second trunk line extending between said repeater and said automatic switch and comprising a pair of line conductors; said first trunk line, said repeater, said second trunk line and said automatic switch being adapted to be connected in tandem in the order named in establishing a connection between two of said telephone stations; means included in said repeater and responsive to a seizing pulse of alternating current transmitted over said first trunk line to said repeater for initiating the operation of said stepping switch, means controlled by said stepping switch for releasing said repeater in the event at least one pulse of alternating current, following said alternating current seizing pulse, is not transmitted over said first trunk line to said repeater before said stepping switch is operated to a predetermined off-normal position, means included in said repeater and responsive to relatively short alternating current pulses transmitted over said first trunk line to said repeater for arresting the operation of said stepping switch and for transmitting corresponding direct current impulses over said second trunk line to said automatic switch, whereby said automatic switch is caused to operate to select the called one of said telephone stations, a normally incomplete path for impressing a predetermined potential upon one of said line conductors, means included in said repeater and responsive to a relatively long supervisory pulse of alternating current transmitted over said first trunk line to said repeater for again initiating the operation of said stepping switch and for preparing a point in said path, means operative to complete said path for an interval following the end of said alternating current supervisory pulse and to arrest the last-mentioned operation of said stepping switch, means included in said automatic switch and responsive to the completion of said path for completing a talking connection to said called telephone station when said called telephone station is busy, means included in said repeater and responsive to a release pulse of alternating current of greater duration than said supervisory pulse and transmitted over said trunk line to said repeater for causing said stepping switch to operate to a predetermined off-normal position, and means operative in response to the operation of said stepping switch to said predetermined off-normal position for causing said repeater to be released.

33. In a telephone system, a plurality of telephone stations, a repeater, a pair of trunk lines extending to said repeater, each of said trunk lines including a pair of line conductors, a source of direct current, the conductors of one of said trunk lines being connected directly to the terminals of said source, the conductors of the other of said trunk lines also being connected to the terminals of said source, a control relay operative when a call routed by way of said repeater is answered at a called one of said telephone stations, and means responsive to operation of said control relay for reversely connecting the line conductors of said other trunk line to the terminals of said source without disturbing the connections between the line conductors of said one trunk line and said source.

34. In a telephone system, a plurality of telephone stations, a repeater, a pair of trunk lines extending to said repeater, each of said trunk lines including a pair of line conductors, a source of direct current, a line relay including a pair of windings, circuit conductors connecting the conductors of said trunk lines to opposite terminals of said source through the windings of said line relay, a control relay operative when a call routed by way of said repeater is answered at a called one of said telephone stations, and means responsive to operation of said control relay for reversely connecting the conductors of one of said trunk lines to the terminals of said source without disturbing the connections between the line conductors of the other trunk line and said source.

35. In a telephone system, a plurality of telephone stations, a repeater, a pair of trunk lines extending to said repeater, each of said trunk lines including a pair of line conductors, a line relay including a pair of line terminals the conductors of one of said trunk lines being connected directly to said line terminals, a control relay operative when a call routed by way of said repeater is answered at a called one of said telephone stations, said control relay including a set

70

of contact springs, and circuit connections including said contact springs for connecting the line conductors of said other trunk line to the line terminals of said line relay, said circuit connections being so arranged that the conductors of said other trunk line are reversely connected to said line terminals in response to operation of said control relay.

36. In a telephone system, a repeater, automatic switching apparatus, a trunk line extending between said repeater and said automatic switching apparatus and means for completing a calling circuit to said repeater; said repeater comprising, in combination, means responsive to the completion of said calling circuit for transmitting a seizing pulse of alternating current over said trunk line to said automatic switching apparatus, means responsive to impulses transmitted to said repeater over said calling circuit for causing corresponding pulses of alternating current to be transmitted over said trunk line to said automatic switching apparatus, a stepping switch having a normal position and operative to a plurality of off-normal positions, means responsive to the interruption of said calling circuit for initiating the operation of said stepping switch and for causing a release pulse of alternating current to be transmitted over said trunk line to said automatic switching apparatus, and means responsive to the operation of said stepping switch to a predetermined off-normal position for terminating said alternating current release pulse and for arresting the operation of said stepping switch.

37. In a telephone system, a repeater, automatic switching apparatus, a trunk line extending between said repeater and said automatic switching apparatus and means for completing a calling circuit to said repeater; said repeater comprising, in combination, means responsive to the completion of said calling circuit for transmitting a seizing pulse of alternating current over said trunk line to said automatic switching apparatus, means responsive to impulses transmitted to said repeater over said calling circuit for causing corresponding pulses of alternating current to be transmitted over said trunk line to said automatic switching apparatus, a stepping switch having a normal position and operative to a plurality of off-normal positions, means responsive to the interruption of said calling circuit for initiating the operation of said stepping switch and for causing a release pulse of alternating current to be transmitted over said trunk line to said automatic switching apparatus, and means controlled by said stepping switch for terminating said alternating current release pulse.

38. In a telephone system, a repeater, automatic switching apparatus, a trunk line extending between said repeater and said automatic switching apparatus and means for completing a calling circuit to said repeater; said repeater comprising, in combination, means responsive to the completion of said calling circuit for transmitting a seizing pulse of alternating current over said trunk line to said automatic switching apparatus, means responsive to impulses transmitted to said repeater over said calling circuit for causing corresponding pulses of alternating current to be transmitted over said trunk line to said automatic switching apparatus, a stepping switch having a normal position and operative to a plurality of off-normal positions, said stepping switch including an operating magnet, an operating circuit for said magnet, a plurality of

cyclically operative relays, means responsive to the interruption of said calling circuit for causing a release pulse of alternating current to be transmitted over said trunk line to said automatic switching apparatus, means also responsive to the interruption of said calling circuit for preparing said operating circuit and for initiating the operation of said relays, said relays being connected and arranged to complete said operating circuit during each cycle of operation thereof, whereby operation of said switch is initiated in response to the operation of said last-named means, and means responsive to the operation of said stepping switch to a predetermined off-normal position for terminating said alternating current release pulse and for arresting the operation of said relays, thereby to arrest the operation of said stepping switch.

39. In a telephone system, a repeater, automatic switching apparatus, a trunk line extending between said repeater and said automatic switching apparatus and means for completing a calling circuit to said repeater; said repeater comprising, in combination, a plurality of cyclically operative relays, means responsive to the completion of said calling circuit for initiating the operation of said relays and for causing a seizing pulse of alternating current to be transmitted over said trunk line to said automatic switching apparatus, means controlled by said relays for terminating said alternating current seizing pulse and for arresting the operation of said relays after one cycle of operation thereof is completed, means responsive to impulses transmitted to said repeater over said calling circuit for causing corresponding pulses of alternating current to be transmitted over said trunk line to said automatic switching apparatus, a stepping switch having a normal position and operative to a plurality of off-normal positions, said stepping switch including an operating magnet, an operating circuit for said magnet, means responsive to the interruption of said calling circuit for causing a release pulse of alternating current to be transmitted over said trunk line to said automatic switching apparatus, means also responsive to the interruption of said calling circuit for preparing said operating circuit and for initiating the operation of said relays, said relays being connected and arranged to complete said operating circuit during each cycle of operation thereof following the operation of said last-named means, whereby operation of said stepping switch is initiated, and means responsive to the operation of said stepping switch to a predetermined off-normal position for terminating said alternating current release pulse and for arresting the operation of said relays, thereby to arrest the operation of said switch.

40. In a telephone system, a repeater, automatic switching apparatus, a trunk line extending between said repeater and said automatic switching apparatus and means for completing a calling circuit to said repeater; said repeater comprising, in combination, means responsive to the completion of said calling circuit for transmitting a seizing pulse of alternating current over said trunk line to said automatic switching apparatus, means responsive to impulses transmitted to said repeater over said calling circuit for causing corresponding pulses of alternating current to be transmitted over said trunk line to said automatic switching apparatus, a stepping switch having a normal position and operative to a plurality of off-normal positions, means

controlled over said calling circuit for initiating the operation of said stepping switch and for causing a control pulse of alternating current to be transmitted over said calling circuit to said automatic switching apparatus, means responsive to the operation of said switch to a first predetermined off-normal position for terminating said alternating current control pulse and for arresting the operation of said switch, means responsive to the interruption of said calling circuit for again initiating the operation of said stepping switch and for causing a release pulse of alternating current to be transmitted over said trunk line to said automatic switching apparatus, and means responsive to the operation of said stepping switch to a second predetermined off-normal position for terminating said alternating current release pulse and for arresting the operation of said switch.

41. In a telephone system, a repeater, automatic switching apparatus, a trunk line extending between said repeater and said automatic switching apparatus and means for completing a calling circuit to said repeater; said repeater comprising, in combination, a plurality of cyclically operative relays, means responsive to the completion of said calling circuit for initiating the operation of said relays and for causing a seizing pulse of alternating current to be transmitted over said trunk line to said automatic switching apparatus, means controlled by said relays for terminating said alternating current seizing pulse and for arresting the operation of said relays after one cycle of operation thereof is completed, means responsive to impulses transmitted to said repeater over said calling circuit for causing corresponding pulses of alternating current to be transmitted over said trunk line to said automatic switching apparatus, a stepping switch having a normal position and operative to a plurality of off-normal positions, said stepping switch including an operating magnet, an operating circuit for said magnet, means controlled over said calling circuit for causing a control pulse of alternating current to be transmitted over said trunk line to said automatic switching apparatus, means responsive to the operation of said last-named means for preparing said operating circuit and for initiating the operation of said relays, said relays being connected and arranged to complete said operating circuit during each cycle of operation thereof following the operation of said last-named means, whereby operation of said stepping switch is initiated, means responsive to the operation of said stepping switch to a first predetermined off-normal position for terminating said alternating current control pulse and for arresting the operation of said relays, thereby to arrest the operation of said switch, means responsive to the interruption of said calling circuit for causing a release pulse of alternating current to be transmitted over said trunk line to said automatic switching apparatus, means also responsive to the interruption of said calling circuit for again preparing said operating circuit and for again initiating the operation of said relays, whereby operation of said stepping switch is again initiated, and means responsive to the operation of said stepping switch to a second predetermined off-normal position for terminating said alternating current release pulse and for arresting the operation of said relays.

42. An impulse repeater adapted to be connected to incoming and outgoing trunks and comprising means for transmitting alternating current control pulses of different lengths over one of said trunks, a stepping switch controllable over the other of said trunks, and means comprising said stepping switch for controlling the lengths of at least a portion of said control pulses.

43. An impulse repeater adapted to be connected to incoming and outgoing trunks and comprising means for transmitting alternating current pulses of different lengths over one of said trunks for different control purposes, a stepping switch controllable over the other of said trunks, and means comprising said stepping switch for controlling the lengths of the alternating current pulses transmitted over said one trunk for certain of said control purposes.

44. An impulse repeater adapted to be connected to incoming and outgoing trunks, means for transmitting alternating current control pulses of different lengths to said repeater, and means comprising a stepping switch controlled in accordance with the lengths of said control pulses for effecting predetermined different control operations individually determined by the lengths of said control pulses.

45. An impulse repeater adapted to be connected to incoming and outgoing trunks and comprising means for transmitting alternating current pulses over one of said trunks for different control purposes, a stepping switch controllable over the other of said trunks, means comprising said stepping switch for controlling the lengths of the alternating current pulses transmitted over said one trunk for certain of said control purposes, means for transmitting alternating current pulses of different lengths over said one trunk to said repeater, and means comprising said stepping switch controlled in accordance with the lengths of said last-mentioned pulses for effecting predetermined different control operations individually determined by the lengths of said last-mentioned pulses.

46. In a telephone system, a plurality of telephone stations, a repeater, automatic switching apparatus having access to said repeater over two different paths, means for transmitting current over said paths, and means individual to one of said paths for reversing the direction of current flow over said one path when a call routed by way of said one path and said repeater to a called one of said stations is answered, said last-named means being inoperative to reverse the direction of current flow over the other of said paths.

47. In a telephone system, a plurality of telephone stations, a repeater including two sets of incoming trunk conductors, a selector of one type having access to said repeater over one set of said conductors, a selector of a different type having access to said repeater over the other set of said conductors, means for transmitting current over said conductors, and means individual to one set of said conductors for reversing the direction of current flow thereover when a call routed by way of said one set of conductors and said repeater to a called one of said stations is answered, said last-named means being inoperative to reverse the direction of current flow over the other set of said conductors.

JOHN WICKS.
